UNITED STATES PATENT OFFICE

2,367,634

TELEPHONE SYSTEM

John Wicks, Oak Park, and Harvey W. Balzer,
 Downers Grove, Ill., assignors to Automatic
 Electric Laboratories, Inc., a corporation of
 Delaware

Application December 4, 1942, Serial No. 467,830

56 Claims. (Cl. 179—27)

The present invention relates to telephone systems and, more particularly, to improvements in the apparatus provided in conjunction with two or more toll operator switchboards for setting up toll connections between the toll switchboards and the substations served by different exchanges of a multi-exchange network. In the illustrated embodiment of the invention, two-way trunk circuits are provided which may be seized from any one of three different toll operator switchboards all having different requirements as regards supervisory signaling, impulse repeating and register sender control. Moreover, the trunk circuits are required to repeat switch directing signals in either of two different forms, i. e., simplex or loop, to succeeding automatic switching apparatus requiring the different forms of directive control at the different stages thereof.

Accordingly, it is an object of the present invention to provide a toll trunk circuit which is accessible to two or more switchboards of different types and is provided with facilities capable of working with the call handling facilities of all switchboards to which it is accessible and also of repeating switch directing signals of either of two different forms to succeeding automatic switching apparatus.

It is another object of the invention to provide in a system of the character indicated, a toll trunk circuit which may be seized over different access trunks from either of two toll operator switchboards provided in the same exchange and which is equipped with facilities for preventing the seizure thereof from both switchboards at the same time.

According to another object of the invention, the two toll operator switchboards are provided with facilities of different types for handling toll calls of the same type and provisions are made in the toll trunk circuits commonly accessible thereto, whereby the trunk circuits may be controlled by the call handling facilities provided at either of the two switchboards.

It is a further object of the invention to utilize in a system of the character described, an unbalanced loop circuit condition between a connected trunk circuit and register sender for the purpose of causing the trunk circuit to shift from its signal repeating setting to its supervisory setting after operation of the sender to transmit switch directing signals to the trunk circuit is completed.

It is a further object of the invention to provide a trunk or link circuit of the character described, wherein the facilities for controlling the

type of switch directing signals repeated through the circuit are automatically governed over one of the talking conductors of the trunk to which the signals are repeated.

5 According to another object of the invention, the improved trunk circuit is provided with two relays each capable of repeating received switch directing signals to an associated outgoing trunk, and provisions are made in the circuit for selecting different ones of the two relays for use when the circuit is seized over two different routes respectively utilizing different types of directive control.

It is still another object of the invention to 15 produce supervisory facilities for repeating supervisory signals of like significance but different character over a common supervisory path which may be utilized in connections set up between a called point and either of two calling points, when 20 the same supervisory operation is performed at the called point.

According to still another object of the invention, the character of the supervisory signal transmitted over the common supervisory path 25 is automatically determined in accordance with the originating point of the call.

The invention, both as to its organization and method of operation, together with further objects and advantages thereof, will best be understood by reference to the specification taken in connection with the accompanying drawings in which Figs. 1 and 2, when laid side by side in the order named, illustrate the trunking plan and general arrangement of a telephone system embodying the features of the present invention; and Figs. 3 to 45, inclusive, when assembled in the manner illustrated in Fig. 46, illustrate the details of a system arranged according to the trunking plan of Figs. 1 and 2 and having incorporated therein the features of the invention briefly referred to above.

GENERAL DESCRIPTION OF THE SYSTEM

Referring now more particularly to Figs. 1 and 2 of the drawings, the telephone system there illustrated comprises a central office 10 of the fully automatic type, a remote toll office No. 1, a remote toll office No. 2, a remote manual office No. 1 provided with a switchboard 41, a remote manual office No. 2 provided with a switchboard 42, and an automatic exchange 3. The central office 10 is illustrated as serving a plurality of substations A, B, C, etc., which are connected with the automatic switching equipment of the office by means of lines 44, 45, etc. Each of the

five remote offices also serves a plurality of subscriber substations. It is noted in this regard that the two toll offices and the central office 10 are provided with automatic switching equipment for handling both local calls and inter-office toll calls. The five offices remote from the central office 10 are trunk connected with the central office by means of toll trunks which are utilized exclusively in the handling of toll traffic. Thus the toll office No. 1 is shown as being connected to the central office 10 by means of a trunk 5 which terminates in a trunk circuit 26 in the central office 10. Similarly, the trunks 6, 7, 8 and 2 which respectively terminate in the trunk circuits 27, 28, 29 and 4, are provided for connecting the four other outlying offices with the central office 10. It will be understood in this regard that the number of toll trunks provided to connect the central office 10 with any one of the five outlying offices is determined by the amount of toll traffic between the two offices. For example, if the two illustrated toll offices are geographically situated to handle a large volume of toll traffic involving the central office 10, two or more groups of trunks each including as many as ten trunks may be required between the central office 10 and each of the two toll offices.

The trunks utilized to connect the central office 10 with each of the two illustrated manual offices are of the ring-down type. Accordingly, trunk circuits 28, 29, etc., of the well-known ring-down type are used to terminate these trunks in the central office 10. The trunk circuit 4, which terminates the one-way trunk 2 in the central office 10, is of the automatic to automatic type, being provided with facilities for repeating received dial impulses to the trunk 2 on an outgoing call to the exchange 3.

The automatic switching equipment as provided in the central office 10 is of two different types requiring different forms of directive control. More specifically, the local automatic switching equipment, i. e., that comprising the switch trains 31, 33 and 41, includes selector and connector switches requiring the well-known reverting type of directive control. This form of directive control is commonly used in the two-motion selector and connector switches of the rotary-vertical type conventionally employed in auto-manual systems. Since the details of this local switching equipment form no part of the present invention they have not been illustrated in the drawings. It is noted, however, that the toll switching equipment as provided in the central office and described below is of the well-known Strowger type employing straightforward impulsing or directive control in the setting of the selected switches of a train. Accordingly, provisions are made at certain switching stages of the toll switching equipment for converting straightforward directive control into reverting directive control for the purpose of permitting the toll operators to obtain access to the subscriber substations served by the central office.

In general, the facilities for handling toll calls in the central office 10 and each of the two illustrated toll offices may be identical. It will be understood, therefore, that the following description relative to the toll switching equipment provided in the central office 10 may be considered as applying also to the toll switching facilities as provided in the toll office No. 1 and the toll office No. 2. These facilities as provided in the central office 10 include an eight position toll operator switchboard 11 which is capable of han-

dling toll calls of all types. It is contemplated that each position of this switchboard shall function as a universal position in that both C. L. R. or outward toll calls requiring ticketing, and inward toll calls requiring no ticketing may be handled at any operator position. Facilities are also provided in conjunction with each of the eight operator positions for permitting the operator at any one of these positions to initiate delayed calls in the handling of point to point traffic. The trunking plan of the system also contemplates that all interposition or T.X calls shall be routed to either the first or the second position of the switchboard 11. To this end the illustrated T.X position distributor 14 is limited in its operation to the distribution of calls to the first and second positions of the switchboard 11.

The call handling facilities provided at and in association with each of the eight positions of the switchboard 11 are identical. Briefly considered, these facilities as provided at the No. 1 position of the switchboard comprise an operator position circuit 18, a plurality of links, such, for example, as the link 15, for routing calls to the position circuit 18 and for extending calls from this circuit, and a link distributor 19 for selecting idle ones of the links individual to the No. 1 position of the switchboard for use in a predetermined order. Each of the links provided at the switchboard 11 includes an answer or line finder switch and a call or selector switch. Thus, the illustrated link 15 is shown as comprising an answer switch 16 and a call switch 17. For the purpose of directing the extension of a connection from this position of the switchboard either through the front or the rear end of a link selected by the distributor 19, impulse sending equipment is provided which includes a key set 22, a sender control circuit 20, and a register sender 21 comprising the impulse sender 21A and the digit registers 21B. Two additional register senders 51 and 52 are provided which are common to all positions of the switchboard 11 and may be seized for use from any position when the sender individual to that position is out of order. The details of the sender control circuit 20 and the register sender 21 have been illustrated in the drawings. The key set 22, on the other hand, has been only schematically shown, it being noted in this regard that this key set is of the exact form disclosed in Fig. 16 of Patent No. 2,167,710, granted August 1, 1939, Thomas F. Crocker.

Incoming calls appearing before the various links of the switchboard 11 for answering, are received in trunk circuits which differ slightly in arrangement in accordance with the particular character of the calls. For example, inward toll calls originating in the toll office No. 1 or the toll office No. 2 may be extended to the switchboard 11 for answering through a group of inward trunk circuits, including the trunk circuit 25, or a group of interposition trunk circuits, including the trunk circuit 24. Outward toll calls, on the other hand, appear before the links of the switchboard 11 in C. L. R. trunk circuits of conventional design, one of which is schematically illustrated at 23. In order to preselect the different positions of the switchboard 11 for use in a predetermined order as calls are extended to the trunk circuits appearing before the rear ends of the links provided at the different positions of this switchboard, a position distributor 13 is provided. For the purpose of allotting inward and outward toll calls alternately to the switchboard 11, and the

additional purpose of controlling the position and link start relays of the position and link circuits provided at the different positions of the switchboard 11, a start circuit 12 common to the inward and C. L. R. trunk circuits is provided. This start circuit is also utilized in the extension of calls to the switchboard 11 from the ring-down trunks extending to the manual office No. 1, calls on these trunks being classed in the same category as outward or C. L. R. calls originating in the area served by the central office 10.

In the illustrated trunking plan, three selective or directly controlled switching stages are provided in the toll switching equipment of the central office 10. More specifically, calls incoming from the toll office No. 1, the toll office No. 2 and the manual office No. 2 are first handled at a primary switching stage which includes a group of finder-selector links, one of which is identified at 35 as comprising a finder 36 and a selector 37. For the purpose of allotting these links for use in a predetermined order, a link distributor 39 of conventional design is provided. From these links, calls incoming from the indicated remote offices may either be extended through the local automatic switching equipment comprising the switch train 31, for example, to subscriber substations served by the central office 10, or to the toll operator switchboard 11, or to others of the toll and manual offices remote from the central office 10. In the last-mentioned case, the second switching stage comprising the toll second selector 32, or the second and third toll switching stages comprising both the second selector 32 and the toll third selector 34, may be required to handle the calls. If a call as extended to the link 35, for example, is to be routed through the local automatic switching equipment to a subscriber substation served by the central office 10, the switch directing signals received in the link 35 from the calling point must be converted to the form required to control the local switching equipment of the central office before the call can be routed through this equipment to the desired substation. To this end a group of register senders are provided in association with the links forming the first switching stage of the toll switching equipment. More specifically, the illustrated register sender 40 of this group has the function of converting received switching directing impulses into the revertive type of switch directing signals which are required for control of the local automatic switching equipment in the central office. These register senders are common to the links provided at the primary switching stage of the toll switching equipment and may be seized through register selectors individual to the links. Thus the illustrated link 35 is shown as having associated therewith a register selector 38 through which the register sender 40 may be seized. The register sender 40 and the register selector 38 are preferably of the exact form disclosed and claimed in copending application Serial No. 439,218, filed April 16, 1942, now Patent No. 2,341,879, granted February 15, 1944, to Seth E. Peterson and Vincent A. Johnson.

In the routing of calls from the toll operator switchboard 11 to the remote toll, manual and automatic offices through the front ends of the links provided at this switchboard, the primary and secondary switching stages of the toll switching equipment are not required. It will be noted in this regard that a straight multiple is provided between the contact levels of the toll second selectors and the call switches of the links associ-

ated with the different positions of the switchboard. Depending upon the destination of such calls, however, the toll third selectors, including the selector 34, may be required in order to gain access to the desired group of inter-office trunks. For the purpose of permitting calls to be extended through the rear ends of the links associated with the switchboard 11, i. e., through the answer switches of these links, a group of delayed call selectors, including the selector 47, is provided. These selectors are commonly accessible to all positions of the switchboard 11 through the first level of bank contacts of the answer switch of each link, and a straight multiple is provided between the bank contacts of the delayed call selectors, the toll second selectors, and the call switches of the position links. Thus each position of the switchboard is permitted to have access to the same routes over the front and rear ends of the links provided therewith.

In the handling of inward calls appearing at the switchboard 11, it is necessary to extend the calls to the desired substations through the local automatic switching equipment of the central office. To gain access to this equipment a group of second selectors including the selector 55 are provided, which selectors are directly accessible to the call switches of the position links and to the delayed call selectors. Each selector of this group is similar to the selector 37 in that provisions are made therein for transmitting received switch directing signals through an associated register selector 56 to a register sender 57, having the function of converting the received signals into the form required to control the switches of the local automatic switching equipment.

The trunking plan of the system is such that certain outward or C. L. R. toll calls which require ticketing in the central office 10, and originate in small exchanges of the central office area, are handled at a toll switchboard 30 of the manual type. In order to permit the operators attending this switchboard to gain access to the trunks extending to four of the five illustrated distant offices, this switchboard is trunk connected to the trunk circuits terminating the inter-office toll trunks in the central office 10, and provisions are made in the trunk circuits for guarding the same against seizure from more than one access point at a time.

Referring now more particularly to the equipment provided at the toll operator switchboard 11, the operator position circuit 18 is illustrated in Figs. 29, 30, 31, 32, 33, 40 and 41 as comprising an operator headset including the transmitter 2902 and the receiver 2901, a group of control relays, a group of supervisory lamps, and a group of manually operable keys. The position circuit is arranged to be selectively connected to any one of the links associated therewith by means of the conductors C2563, C2566, C2562, C2561, C2574, C2572, C2571, C2575, C2573, C2579, C2577, C2580, C2568, C2576, C2567, C2578, C2666 and C2569 of the cable 2590, these conductors being multiplied to each of the links associated with the No. 1 position of the switchboard. Talk and monitor repeating coils 2905 and 2906 are provided for associating the operator headset 2901, 2902 with the talking leads extending from the position circuit 18 to the associated links. The relay equipment as provided in this circuit comprises a battery feed relay R2910, an accept call relay R2920, an automatic call answer cut-out relay R2930, a monitor relay R3000, a switching relay R3010, an

all-links-busy relay R3020, a slow-acting link disconnect relay R3030, a call lock relay R3040, a slow-to-release control relay R3050, a position transfer relay R3100, three slow-acting tone relays R3110, R3120 and R3130, a slow-acting impedance cut-off relay R3140, a slow-acting split call relay R3150, a slow-acting split answer relay R3200, a position start relay R3210, a slow-to-release error relay R3220, a control relay R3230, a dial rear lock relay R3240, a sender seize relay R3250, a rear supervisory relay R3260, a slow-to-release control relay R3300, a slow-to-release start relay R3310, a slow-to-release cut-in relay R3320, a pair of dial rear relays R3340 and R3350, and a pair of coin control supervisory relays R4036 and R4038. In general, the usual control keys are provided in the position circuit 18. Briefly considered, these keys comprise a busy key 3046, an operator disconnect key 4005 which is common to the links associated with the position circuit 18, a position transfer key 4015, a delayed call key 4025, four coin control keys 4000, 4010, 4020 and 4030, two ring keys 4040 and 4050, two release keys 4060 and 4070, an emergency start key 4110, a dial rear key 4100, a cut-off rear key 4120, a cut-off front key 4130, two common sender control keys 4140 and 4150, an automatic call answer cut-out key 2908, and an accept call key 2907. It is noted that with the exception of the keys 3046, 4015, 4025, 4109, 4110, 4120, 4130, 4140, 4150 and 2908 all of the keys provided in the position circuit 18 are of the well-known non-locking or self-restoring type. The supervisory signals as provided in the position circuit 18 include the three coin control signal lamps 4034, 4035 and 4126; an answer C. L. R. signal lamp 4121 which is energized to indicate that an incoming toll call is an outward call requiring ticketing; an answer toll signal lamp 4122 which is energized to indicate that an incoming call is of the inward type requiring no ticketing; a pair of common sender lamps 4123 and 4124 which are individual to the register senders 51 and 52, respectively, and are controlled to indicate the idle or busy condition of these senders, and a sender pilot lamp 4125 which may be controlled in accordance with the operation of any one of the senders 21, 51 and 52 to route a call from the No. 1 position of the switchboard to a desired destination. The links associated with the different positions of the switchboard 11 are identical in arrangement. In this regard it is noted that the call switch 17 as provided in the illustrated link 15 may be of the form disclosed in the above-cited Patent No. 2,167,710 of Thomas F. Crocker, except as modified in the respects explained below. The answer switch of this link is illustrated in Figs. 24, 25 and 26A of the drawings as including a Strowger switching mechanism, a group of control relays and three supervisory lamps 2516, 2603 and 2604. More specifically, the front supervisory lamp 2516 is arranged to be controlled from and through the call switch 17; the rear supervisory lamp 2603 is arranged to be controlled from and through the answer switch 16; and the busy lamp 2604 is controlled locally in the link 15 to provide an indication of the progress of a call through the link 15 and an indication that this link is occupied with a call. Briefly considered, the Strowger switching mechanism provided in the answer switch 16 has a line or trunk capacity of 200 lines and includes the usual contact field which is divided into ten levels of ten contact sets each; wipers 2401 to 2408, inclusive, which are adapted to be positioned on the contacts of a selected contact set in any

level; a vertical test contact set 2410 which, in conjunction with the test wiper 2409, is utilized to control the vertical movement of the wipers 2401 to 2408, inclusive; a vertical magnet 2411 for elevating the enumerated wipers to a position opposite a desired level of contacts; a rotary magnet 2412 for rotating the enumerated wipers until they engage the contacts of a desired contact set; a release magnet 2501; four sets of vertical off-normal springs 2414, 2504, 2503 and 2502; two sets of left normal post springs 2419 and 2420 which are operated when the wipers 2401 to 2408, inclusive, are elevated to a position opposite the first level of contacts in the associated contact field; a set of right normal springs 2605 which is operated when the enumerated wipers are elevated to one or more positions opposite one or more predetermined levels of contacts in the associated contact field; and three sets of cam springs 2418, 2658 and 2659, all of which are operated when the wipers 2401 to 2408, inclusive, are rotated to the eleventh off-normal positions thereof after searching across an entire level of contacts in the associated contact field. The relay equipment provided in the answer switch 16 includes a pair of line test relays R2430 and R2450, two switching relays R2440 and R2460, a stepping relay R2470, a slow-to-operate change-over relay R2480, a release rear relay R2510, a rear supervisory relay R2520, a link start relay R2530, a pair of connect relays R2560 and R2630, a front supervisory relay R2600, a blocked sender relay R2610, a cut-through relay R2620, a second rear supervisory relay R2640, and a start send relay R2650. In addition to the control equipment just described, the answer switch 16 includes a monitor key 2540 of the locking type which may be manually operated to effect the setting up of a monitoring connection between the position circuit 18 and a talking circuit as established through the link 15 between two subscriber substations. The link further includes a talk key 2550 of the non-locking or self-restoring type which may be manually operated to effect a connection between the link 15 and the position circuit 18 over which all required talking and supervisory operations may be effected.

As previously indicated, a link distributor circuit is provided in association with each of the positions of the switchboard for preselecting idle ones of the associated links for use in a predetermined order. These distributors are identical in arrangement. Briefly considered, the illustrated distributor 19 associated with the No. 1 position of the switchboard 11 comprises a slow-to-release reset relay R3800 and a plurality of link relays R3810, R3820, R3830, etc., individual to the several links associated with the first position of the switchboard.

Each position circuit of the switchboard 11 also has individually associated therewith a sender control circuit having the function of controlling either the register sender individual to the associated position or a selected one of the two common senders 51 and 52. The sender control circuit 20 as provided in association with the position circuit 18 is illustrated in Figs. 34, 35, 36 and 37 of the drawings as including a connect relay R3400, a slow-to-release error relay R3410, a dial rear relay R3420, a slow-to-operate sender start relay R3430, six supervisory relays R3440, R3500, R3510, R3520, R3530 and R3540, a control relay R3600, a release relay R3610 of the slow-to-release type, a hold relay R3620 also of the slow-to-release type, a sender disconnect

relay R3630, a sender supervisory relay R3640, a sender connect relay R3700, a pair of transfer relays R3710 and R3720, and two common sender distributor relays R3730 and R3740. Additional common sender distributor relays individual to the second to eighth positions of the switchboard 11 are indicated in the lower right-hand portion of Fig. 37 of the drawings. The sender control circuit 20 may be operatively associated with the position circuit 18 and a selected one of the links associated with this position circuit by means of the conductors entering the cable 3425. It may be connected to the keys of the key set 22 by means of the conductors entering the cable 3760. This control circuit is normally connected to the register sender 21 by means of the conductors entering the cable 3765 and may be selectively connected to either of the two common register senders 51 and 52 by means of the conductors respectively entering the two cables 3766 and 3767.

As shown in Figs. 42 to 45, inclusive, of the drawings, the register sender 21 comprises a group of digit registers 21B and an impulse sender 21A. The digit registers are identical in arrangement, each including a connect relay, four code relays and three control relays. Thus the first register is illustrated as comprising a connect relay R4470, four code relays A1, B1, C1 and D1, a release relay R4400, a sequence relay R4410, and a transfer relay R4420. The corresponding relays of the illustrated second and third registers may be readily identified by comparison with the relays of the described first register. Briefly considered, the impulse sender 21A comprises a pair of transfer relays R4200 and R4270, five impulse counting relays R4210, R4220, R4230, R4240 and R4250, a reflex relay R4260, a stop relay R4280, two digit space relays R4290 and R4300, a stop send relay R4310, three pulse generating relays R4315, R4320 and R4330, a transfer relay R4340, a start relay R4350, a start send relay R4360, and a slow-acting hold relay R4380.

The pieces of equipment thus far considered in some detail are all individual to the first position of the switchboard 11 and are only utilized in the handling of calls routed to this position of the switchboard. The common start circuit 12 the position distributor 13 and the position distributor 14, on the other hand, are common to two or all of the positions of the switchboard and are directly utilized in the routing of calls to the switchboard. Briefly considered, the operator position distributor 13 comprises a slow-to-release reset relay R3900, and position relays R3910, R3920, R3930, etc., individual to the eight positions of the switchboard. The T. X operator position distributor 14, on the other hand, includes only two distributor relays R3940 and R3950 which are individual to the first and second positions of the switchboard and are respectively operative to select the corresponding operator positions to receive incoming inter-position trunk calls.

As previously indicated, the common start circuit 12 has the function of controlling the position start relays of the position circuits selected by the distributor 14 to receive calls, and the additional function of alternately allotting inward and outward toll calls to the different positions of the switchboard 11. In brief, this circuit comprises a pair of differentially wound change call relays R2710 and R2720, a control relay R2730, a start relay R2740, a toll or inward relay

R2750, and a C. L. R. or outward relay R2760. It also includes a plurality of C. L. R. level relays R2820, R2830, etc., individual to the contact levels of the answer switches through which access is gained to the C. L. R. and ring-down trunk circuits to which outward toll calls may be routed from the subscriber lines of the system; a group of inward toll level relays R2890, R2800, etc., individual to the contact levels of the answer switches through which access may be gained to the inward trunk circuits appearing before the links of the switchboard 11; a slow-to-operate toll lockout relay R2810; and a slow-to-operate C. L. R. lockout relay R2815. This circuit is arranged to be controlled over the start leads extending to the inward, C. L. R. and ring-down trunk circuits through which calls are extended to the switchboard 11, these start leads being connected to the trunk circuits through the cable 2806. It is also connected to the vertical test contact sets 2410, etc., of the answer switches provided at the operator switchboard 11 by means of the level marking leads entering the cable 2806. It is connected to the operator position distributor 13 and to the supervisory lamps 4121 and 4122 of each position circuit 18 by means of the conductors entering the cable 2807.

The trunk circuits through which calls may be routed to the operator switchboard 11 are, for the most part, of entirely conventional design. Thus the ring-down trunk circuits 28 and 29, the automatic to automatic trunk circuit 4, the inter-position trunk circuit 24, and the C. L. R. trunk circuit 23 may be in all essential respects similar to the corresponding trunk circuits disclosed in the above-cited patent to Thomas F. Crocker. It is noted, however, that facilities similar to those included in the trunk circuits 26 and 27 are provided in the inter-position trunk circuit 24 and the ring-down trunk circuits 28 and 29 for permitting the operators at the toll switchboard 30 to gain access to the switchboard 11 and to the trunks extending to the manual office No. 1 and the manual office No. 2.

The inward trunk circuit 25 through which inter-office toll calls may be routed to the switchboard 11 is illustrated in Fig. 23B of the drawings as comprising a repeating coil 2383 and a group of control relays. More specifically, the relays of this trunk circuit include four control relays R2350, R2360, R2365 and R2375, the first of which is of the slow-to-operate type, a seizure relay R2370, an alternating current rering relay R2380, and a slow-to-operate cut-off relay R2390. This trunk circuit is accessible to the selectors of the toll switching equipment over an incoming trunk 25f and to the answer switches of the links provided at the switchboard 11 over an outgoing trunk 25d.

The trunk circuits 26 and 27 which respectively terminate the toll trunks 5 and 6 extending to the toll office No. 1 and the toll office No. 2, are identical in arrangement. Accordingly, corresponding circuit elements of the two trunk circuits have been identified in the drawings by reference numerals which differ only in the first two digits thereof, the tens and units digits of the reference numerals identifying corresponding parts being the same in both circuits. Briefly considered, the trunk circuit 26 is illustrated in Figs. 3B, 4, 5, 6 and 7 of the drawings as comprising a pair of tandem related repeating coils 304 and 310, the first of which terminates the conductors of the trunk 5, and a group of control

relays. More specifically, the relay equipment of this trunk circuit comprises a signal relay R320, a supervisory relay R410, a slow-to-operate digit relay R420, a pair of switching relays R430 and R440, three control relays R450, R460 and R470, an alternating current rering relay R480, a pair of slow-to-release rering control relays R510 and R520, a control relay R530, a supervisory relay R540, a transfer relay R550, a slow-acting transfer slave relay R560, a differential slave relay R570, a simplex pulsing relay R580, a loop pulsing relay R610, a differential relay R620, a switching relay R630, a seizure relay R640, a slow-to-release loop seizure relay R650, a pulsing relay R660, a slow-acting simplex slave relay R670, a 15 simplex relay R680, a slow-acting hold relay R710, a hold slave relay R720, a slow-acting digit relay R730, a bridge slave relay R740, a cut-off relay R750, a seizure relay R760, and a dial relay R770. The corresponding circuit elements of the trunk circuit 27 may be readily identified by a comparison of this trunk circuit with the described trunk circuit 26. In this regard it is noted that the trunk circuits 26 and 27 are arranged to gain access to the links forming the first toll 10 switching stages of the central office over the trunks 26d and 27d. These two trunk circuits are respectively accessible to the toll second 15 selectors of the central office 10 over the trunks 26f and 27f respectively. They are also accessible to the toll switchboard 30 over the trunks 26n and 27n, respectively.

The equipment as provided at the toll switchboard 30 is illustrated for reference purposes only and is not intended to represent an arrangement which will normally be utilized in commercial practice. Briefly considered, the illustrated equipment comprises an operator position circuit 341, a connect key 355 for operatively associating the position circuit 341 with the trunk 27n, a call key 346 over which the trunk circuit 27 may be seized, a supervisory lamp 345 for indicating the idle or busy condition of the trunk circuit 27, a calling device 342 of the conventional dial-operated type, position and trunk connect keys 343 and 344, a digit relay R350, and a pulsing relay R360. This equipment as described may, for the most part, only be utilized in controlling the illustrated trunk circuit 27.

As previously indicated the finders, including the finder 36, provided at the first switching stage of the toll switching equipment in the central office, are of the well-known Strowger type and may be of conventional circuit arrangement. The selectors provided in association with these finders are also of the Strowger type, the selector 37 being illustrated in Figs. 13, 14, 15 and 16 of the drawings. Briefly described, this selector comprises a switching mechanism of the two-motion type having a contact field divided into ten levels of contact sets each, a set of wipers 1651 to 1654, inclusive, a vertical magnet 1406, a rotary magnet 1450, a release magnet 1310, vertical off-normal springs 1314, 1407, 1408 and 1432, left normal post springs 1454 and 1455, and cam springs 1409, 1616 and 1617. This selector further includes a repeating coil 1550 which may be included in a connection set up through the wiper to a succeeding trunk circuit or selector. The control equipment of the selector comprises a line relay R1320, a slow-acting hold relay R1330, a slow-acting transfer relay R1400, a test relay R1410, a step relay R1420, a cut-in relay R1430, a local call relay R1440, a hold slave relay R1510,

5 a switching relay R1520, a pair of control relays R1530 and R1540, an answer relay R1560, a switching relay R1600, all-trunks-busy relays R1610 and R1620, a control relay R1630, and a slow-to-operate busy relay R1640.

The selectors provided at the second directly controlled switching stage of the toll switching equipment provided in the central office 10 is somewhat similar to the selectors provided at the first stage of this equipment, except that facilities have been provided in the second selectors for automatically transmitting ringing signals to selected trunk circuits of the ring-down type. Briefly considered, the toll second selector 32 is illustrated in Figs. 17 to 20, inclusive, of the drawings as comprising a Strowger switching mechanism, a repeating coil 2020, a minor switch 2040 which is utilized to time the duration of transmitted ringing signals, and a group of control relays. More specifically, the Strowger switching mechanism comprises the usual contact field, wipers 2051 to 2056, inclusive, associated with the contact field, a vertical magnet 1817, a rotary magnet 1870, a release magnet 1748, vertical off-normal springs 1747, 1748 and 1801, left normal post springs 1803, right normal post springs 1915, and eleventh step cam springs 1802, 1951, 1952 and 2013. The minor switch 2040 is of the eleventh point type and includes a single set of contacts, a wiper 2045, an operating magnet 2041, a release magnet 2042, and off-normal springs 2043 and 2044. The control equipment of the selector 32 comprises a test relay R1700, an all-trunks-busy relay R1710, a switching relay R1720, a line relay R1730, a slow-acting hold relay R1740, a pair of slow-acting transfer relays R1810 and R1830, two additional transfer relays R1820 and R1860, control relays R1840, R1900, R1910 and R1920, a switching relay R1930, two ringing control relays R1940 and R2000, a rering relay R2010, and a ringing relay R2030.

The toll third selector 34 as provided at the third directly controlled switching stage of the toll switching equipment in the central office 10, is substantially similar to the selectors of the second switching stage, except that the facilities for signaling ring-down trunks have been omitted therefrom. In brief, the toll third selector 34 is illustrated in Figs. 21, 22 and 23A of the drawings as comprising a Strowger switching mechanism and a group of control relays. More specifically, the switching mechanism of this selector comprises the usual contact field, wipers 2341 to 2346, inclusive, a vertical magnet 2217, a rotary magnet 2260, a release magnet 2146, vertical off-normal springs 2147, 2201 and 2202, left normal post springs 2218, right normal post springs 2312, and eleventh step cam springs 2117 and 2203. The control relays of this selector include a test relay R2100, an all-trunks-busy relay R2110, a switching relay R2120, a line relay R2130, a slow-acting hold relay R2140, a pair of slow-acting transfer relays R2210 and R2230, an additional transfer relay R2220, and five control relays R2240, R2250, R2300, R2310 and R2320.

As previously pointed out, the second selector 35 and the corresponding selectors accessible to the call switches of the links provided at the switchboard 11 are utilized in the extension of connections through the revertively controlled local switches of the central office to subscriber substations served by this office. This selector may be of the same form as the toll first selector 37 illustrated in Figs. 13, 14, 15 and 16 of the

drawings. The delayed call selectors, including the selector 47, are provided for permitting the operators attending the switchboard 11 to route calls through the answer switches of the links provided at this switchboard. If desired, the illustrated delayed call selector 47 may be of the same character as the toll first selector disclosed in Fig. 7 of the above-cited patent to Thomas F. Crocker.

In addition to the equipment described above, the central office 10 includes the usual equipment common to the switching links of this office for supplying the required power and signal voltages. This equipment includes the exchange battery, sources of coin control potential, tone and ringing current generators and the usual supervisory apparatus. It also includes the impulse generating commutator elements 2685 and 2686 which are driven at constant speeds of 120 and 160 revolutions per minute, respectively.

In considering the operation of the system, the manner in which toll calls of different types may be handled at the first position of the switchboard 11 is first disclosed. Following this explanation the mode of handling calls between the various toll offices is taken up for consideration.

PREPARING AN OPERATOR POSITION TO RECEIVE CALLS

In order to unguard an operator position in the position distributors 13 and 14, thereby to render the position accessible to the lines and trunks terminating at the central office, the plug of the operator headset at that position is inserted in the jack of the position circuit. Thus to condition the illustrated first position to receive incoming calls the headset plug 2903 is inserted in the position circuit jack 2904. In response to this operation the receiver 2901 is bridged across the upper left-hand winding of the repeating coil 2905 and the transmitter 2902 is bridged across the lower winding of this repeating coil in series with the exchange battery and the winding of the battery feed relay R2910. When thus energized the relay R2910 closes its contacts 2912 to prepare a circuit for energizing the automatic call cut-out relay R2930. At its contacts 2913, the relay R2910 prepares the operating circuit for the accept call relay R2920. At its contacts 2915, the relay R2910 completes an obvious path for impressing ground potential upon the lead C4132, thereby to prepare various operating circuits described more fully below. At its contacts 2914, the relay R2910 completes the operating circuit for the all-links-busy relay R3020. This circuit includes branches individually controlled by the relays of the links that are provided for the exclusive use of the first operator position. For example, one branch of this circuit extends from ground by way of the contacts 2512, 2444, 2464, 2481 and 2627, C3045, the contacts 2914, the winding of R3020, the contacts of the busy key 3046, and the contacts 3105' to battery. Similar branches of this circuit extend from the lead C3045 to ground in each of the other links individual to the No. 1 operator position. At its contacts 2911, the relay R2910 prepares the operating circuit for the start relay R3310, and various other circuits described below.

The all-links-busy relay R3020, upon operating, closes its contacts 3022 and 3023 to complete circuits over which the link distributor 19 is controlled to allot one of the links individual to the No. 1 operator position to handle the first call

75 routed to this position, in the manner explained below. At its contacts 3021, the relay R3020 completes the prepared operating circuit for the start relay R3310, this circuit extending from ground by way of the contacts 2911, 3021, 3033, 3104', 3223, 3231, 3256 and 2931, C3364, the contacts of the delayed call key 4025, C4091, the winding of R3310, and the contacts 3349 to battery.

When thus energized, the start relay R3310 closes its contacts 3312 to prepare a locking circuit for the accept call relay R2920. At its contacts 3313, the relay R3310 disconnects the position guard lead C3962 from ground, thereby to mark the position circuit 18 as idle in the position distributor 13. At its contacts 3311, the relay R3310 prepares a circuit for energizing the position start relay R3210 in series with the start relay R2740 of the common start circuit 12. At its contacts 3314, the relay R3310 completes an obvious path for impressing ground potential upon the distributor start lead C3963.

Distributing links to the first operator position

As indicated above, the all-links-busy relay R3020, upon operating, causes the link distributor 19 to select the first link individual to the No. 1 operator position to handle the first call routed to this position. To this end the relay R3020 in closing its contacts 3022 completes a circuit for energizing the distributor relay R3810 individual to the first link 15 associated with the No. 1 operator position. This circuit extends from ground by way of the contacts 2911, 3022 and 3802, and the left winding of R3810 to battery. 35 When thus energized the relay R3810 locks up in a circuit which includes its right winding, the contacts 3814 and 3825, the winding of R3800, and the contacts 3022 and 2911. The relay R3800 operates when energized in this circuit. At its contacts 3815, the relay R3810 opens a point in the locking circuit for the distributor relay R3830 individual to the last link associated with the No. 1 operator position. At its contacts 3812, the relay R3810 opens a point in the operating circuit for the third distributor relay in the chain. At its contacts 3813, the relay R3810 prepares the operating circuit for the second distributor relay R3820. At its contacts 3811, the relay R3810 prepares the operating circuit for the connect relay R2630 of the first link 15. The relay R3800, upon operating, closes its contacts 3801 further to prepare the operating circuit for the connect relay R2630 of the link 15. At its contacts 3802, the relay R3800 opens a point in the above-traced operating circuit for the first distributor relay R3810.

When a call is subsequently routed to the No. 1 operator position in the manner explained below, one of the two switching relays R2440 and R2460 is operated in the link circuit 15 to complete the prepared operating circuit for the second link relay R3820, this circuit extending from ground by way of the contacts 2443' or 2463', the guard lead C3842, the contacts 3813 and 3833, and the left winding of the second distributor relay R3820 to battery. When thus energized, the relay R3820 locks up in a circuit which includes the contacts 3824 and 3835, the winding of R3800, and the contacts 3022 and 2911. At its contacts 3825, the relay R3820 deenergizes the first distributor relay R3810. At its contacts 3823, the relay R3820 prepares the operating circuit for the third distributor relay over a path which includes the guard conductor C3852 extending to the second link associated with the No. 1 operator

position. At its contacts 3822, the relay R3820 opens a point in an alternative operating circuit for the first distributor relay R3810. At its contacts 3821, the relay R3820 prepares a circuit including the start lead C3851 for energizing the connect relay provided in the second link associated with the No. 1 operator position.

The first distributor relay R3810, upon restoring, closes its contacts 3815 to prepare the locking circuit for the succeeding distributor relay R3830, and opens its contacts 3814 further to interrupt its own locking circuit. At its contacts 3813, the relay R3810 opens a point in the operating circuit for the second distributor relay R3820. At its contacts 3812, the relay R3810 further prepares the operating circuit for the third distributor relay R3830. At its contacts 3811, the relay R3810 opens a point in the operating circuit for the connect relay R2630 of the illustrated link 15.

When another call is subsequently routed to the No. 1 operator position through the second link individual to this position and one of the switching relays of the second link operates, a circuit including the guard lead C3852 individual to the second link is completed for energizing the third distributor relay R3830. This relay, in operating, locks to ground through its contacts 3834 and the winding of the reset relay R3800; opens its contacts 3835 to deenergize the second distributor relay R3820; opens its contacts 3833 further to interrupt the operating circuit for the relay R3820; closes its contacts 3831 to prepare a circuit over the start lead C3861 for energizing the connect relay of the third link associated with the No. 1 operator position; and closes its contacts 3832 to prepare the above-mentioned alternative operating circuit for the first distributor relay R3810.

The second distributor relay R3820, upon restoring, closes its contacts 3825 to reprepare the locking circuit for the first distributor relay R3810; opens its contacts 3824 further to interrupt its own locking circuit; opens its contacts 3823 to interrupt the operating circuit for the third distributor relay R3830; closes its contacts 3822 further to prepare the alternative operating circuit for the first distributor relay R3810; and opens its contacts 3821 further to interrupt the operating circuit for the connect relay of the second link.

When a call is subsequently routed through the third link to the No. 1 operator position, the guard lead C3862 is connected to ground in this link to complete the alternative operating circuit for the first distributor relay R3810, this circuit also including the contacts 3832, 3822 and 3023. In operating, the relay R3810 performs the functions described above including that of deenergizing the third distributor relay R3830. The latter relay, upon restoring, closes its contacts 3835 to reprepare the locking circuit for the second distributor relay R3820; opens its contacts 3834 further to interrupt its own locking circuit; closes its contacts 3833 to prepare the operating circuit for the second distributor relay; opens its contacts 3832 to interrupt the alternative operating circuit for the first distributor relay; and opens its contacts 3831 further to interrupt the operating circuit for the connect relay of the third link.

The distributor relays continue sequentially to operate in the manner explained above so long as any of the links associated with the No. 1 operator position are idle. In this regard it will be understood that a link is passed over in the

allotting sequence in the event it is occupied with a call at the time its turn for assignment is reached. Thus if the second link is still occupied with a call at the time ground potential is applied to the link guard lead C3842 in the first link 15, but the third link associated with the No. 1 operator position is idle at this time, the second distributor relay R3820 only remains operated for an interval of sufficient length to cause the release of the first distributor relay R3810 and the operation of the third distributor relay R3830. Under these circumstances the guard lead C3852 is connected to ground in the second link associated with the No. 1 operator position so that when the first distributor relay R3810 releases the operating circuit for the third distributor relay R3830 is completed through the contacts 3812 and 3823. In operating, the third distributor relay R3830 deenergizes the second distributor relay and otherwise arranges the link start circuits so that the next incoming call will be routed to the position circuit 18 through the third link. In a manner similar to that just described, any busy one of the other links may be by-passed by the distributor 19 in the selection of a link for extending a call to the position circuit 18.

Although the distributor 19 is shown as including facilities only sufficient to distribute three links to the first position of the switchboard 11, it will be understood that additional distributor relays may be included in the distributor for the distribution of any desired number of links to the position circuit 18, if required. The manner in which the additional relays may be wired into the circuit between the second relay R3820 and the third relay R3830 will be clearly apparent from the above explanation.

If all of the links associated with the No. 1 operator position become busy at the same time, all of the above-described branch paths over which the lead C3045 is normally connected to ground are opened in the links to cause the de-energization and release of the all-links-busy relay R3020. This relay, upon restoring, opens its contacts 3022 and 3023 to deenergize the reset relay R3800 and any operated ones of the distributor relays. At its contacts 3021, the relay R3020 opens a point in the operating circuit for the start relay R3310, causing the latter relay to restore, if operated. In releasing, the relay R3310 connects the position guard lead C3962 to ground through its contacts 3313, thereby to mark the No. 1 position of the switchboard as busy in the position distributor 13. At its contacts 3314, the relay R3310 disconnects the start lead C3963 from ground in the position circuit 18. At its contacts 3311, the relay R3310 opens a point in the circuit for energizing the start relay R3210 in series with the start relay R2740 of the common start circuit 12. Thus it will be noted that when the all-links-busy relay R3020 restores in response to an all-busy condition of the links associated with the No. 1 operator position, this position is marked as busy in the position distributor 13 and cannot be allotted to receive a call. When the all-busy condition of the links is terminated, due to the release of one of the links occupied with a call, the relay R3020 is again energized and recloses its contacts 3021 to recomplete the operating circuit for the start relay R3310. At its contacts 3022 and 3023, the relay R3020 re-completes the initially traced operating circuit for the first distributor relay R3810 and reprepares the alternative operating circuit for this distributor relay.

In operating, the relay R3810 locks to ground through the winding of the reset relay R3800, whereby the latter relay is caused to operate. In the present case the distributor relays operate in sequence successively to test the associated links until that link which has been released is found. For example, if the second link is released to terminate the all-busy condition, the guard lead C3852 is disconnected from ground to prevent the third distributor relay R3830 from being energized when the second distributor relay R3820 operates and the first distributor relay R3810 restores. Accordingly, the second distributor relay R3820 is allowed to remain in its operated position wherein the second link associated with the No. 1 operator position is selected for use.

From the foregoing explanation it will be understood that after the plug 2903 is inserted in the jack 2904 to cause the operation of the three relays R2910, R3020 and R3310 and the link distributor 19 has operated to select the first link 15 for use in routing a call to the operator position circuit 18, the No. 1 position of the switchboard is fully conditioned to receive an incoming call.

ALLOTTING THE OPERATOR POSITIONS FOR USE

As indicated above, when an operator at any position inserts the plug of her headset cord into the jack of the associated position circuit, the distributor start lead C3963 is connected to the ground in that circuit. Thus when the start relay R3310 operates in the position circuit 18, it connects the start lead C3963 to ground through its contacts 3314, and opens its contacts 3313 to disconnect the guard lead C3962 from ground and thus mark the No. 1 operator position as idle in the position distributor 13. When the start lead C3963 is initially connected to ground, a circuit including this lead and the contacts 3901 is completed for energizing the distributor relay R3910. In operating, this distributor relay locks up in a circuit which includes the contacts 3912 and 3924, and the winding of the reset relay R3900. The relay R3900 operates when energized in this circuit. At its contacts 3911, the relay R3910 prepares the previously mentioned circuit for energizing the position start relay R3210 in series with the start relay R2740 of the common start circuit 12. At its contacts 3913, the relay R3910 prepares the operating circuit for the second distributor relay R3920. At its contacts 3914, the relay R3910 opens a point in the operating circuit for the third distributor relay R3930. At its contacts 3915, the relay R3900 opens a point in the locking circuit for the third distributor relay R3930. The reset relay R3900, upon operating, opens its contacts 3901 to interrupt the circuits common to the various operator positions over which the first distributor relay R3910 may be energized. With the relays R3900 and R3910 operated in the position distributor 13, the illustrated first position of the switchboard 11 is allotted for use.

When a call is subsequently extended to the No. 1 operator position through a selected one of the links associated therewith, the start relay R3310 included in the position circuit 18 is de-energized and restores. In releasing, this relay opens its contacts 3311 to interrupt the circuit for energizing the position start relay R3210 in series with the start relay R2740 of the common start circuit 12. At its contacts 3314, the relay R3310 disconnects the distributor start lead C3963 from ground in the position circuit 18. At its contacts

3313, the relay R3310 connects the guard lead C3962 to ground, thereby to complete the prepared circuit through the contacts 3913 and 3933 for energizing the second distributor relay R3920. In operating, the relay R3920 locks to ground through the contacts 3923 and 3924, and the winding of the reset relay R3900. At its contacts 3922, the relay R3920 opens a point in an alternative operating circuit for the first distributor relay R3910. At its contacts 3921, the relay R3920 prepares a circuit including the start lead C3927 for energizing the start relay R2740 in series with the position start relay of the position circuit associated with the No. 2 operator position. At its contacts 3924, the relay R3920 opens the locking circuit for the first distributor relay R3910. At its contacts 3925, the relay R3920 prepares the operating circuit for the third distributor relay R3930. The first distributor relay R3910, in releasing, opens its contacts 3911 further to interrupt the circuit for energizing the position start relay R3210 in series with the start relay R2740 of the common start circuit 12. At its contacts 3912, the relay R3910 opens another point in its own locking circuit. At its contacts 3913, the relay R3910 interrupts the operating circuit for the relay R3920. At its contacts 3914, the relay R3910 further prepares the operating circuit for the third distributor relay R3930. At its contacts 3915, the relay R3910 prepares the locking circuit for the third distributor relay.

When a call is subsequently routed to the No. 2 position of the switchboard, the guard lead C3926 is connected to ground in the position circuit for this operator position, thereby to energize the third distributor relay R3930 through the contacts 3925 and 3914. In operating, the relay R3930 locks to ground through the winding of the reset relay R3900 and the contacts 3915 and 3935. At its contacts 3934, the relay R3930 deenergizes the second distributor relay R3920. At its contacts 3933, the relay R3930 opens another point in the operating circuit for the second distributor relay R3920. At its contacts 3932, the relay R3930 prepares the alternative operating circuit for the first distributor relay R3910. At its contacts 3931, the relay R3930 prepares a circuit for energizing the position start relay of the position circuit associated with the No. 3 operator position in series with the start relay R2740 of the common start circuit 12.

The second distributor relay R3920, in releasing, opens its contacts 3925 to interrupt the operating circuit for the third distributor relay R3930; closes its contacts 3924 to reprepare the locking circuit for the first distributor relay R3910; opens its contacts 3923 further to interrupt its own locking circuit; closes its contacts 3922 further to prepare the alternative operating circuit for the first distributor relay R3910; and opens its contacts 3921 further to interrupt the circuit for energizing the start relay R2740 in series with the position start relay individual to the second operator position.

When the next call to the toll operator switchboard is received the start relay R2740 of the common start circuit 12 is energized in series with the position start relay of the third position over a circuit which includes the start lead C3929 extending to that position. Thus the call is routed to the third position of the switchboard. Incident to this operation, the guard lead C3928 is connected to ground in the position circuit of the third operator position, thereby to energize the first distributor relay R3910 in a circuit which includes the contacts 3922 and 3932. This relay, in

operating, locks to ground through its contacts 3912 and the winding of the reset relay R3900; closes its contacts 3911 to prepare a circuit for energizing the position start relay R3210 in series with the start relay R2740 of the common start circuit 12; closes its contacts 3913 to reprepare the operating circuit for the second distributor relay R3920; opens its contacts 3915 to deenergize the third distributor relay R3930; and opens its contacts 3914 to interrupt the operating circuit for the last-mentioned relay. In releasing, the relay R3930 opens its contacts 3935 further to interrupt its own locking circuit; closes its contacts 3933 and 3934 to reprepare the locking and operating circuits for the relay R3920; opens its contacts 3932 to interrupt the operating circuit for the first distributor relay R3910; and opens its contacts 3931 to interrupt the circuit for energizing the start relay R2740 in series with the position start relay individual to the third operator position of the switchboard.

From the above explanation it will be understood that the position distributor relays are sequentially operated in order successively to select different ones of the operator positions at the switchboard 11 to receive the calls incoming to this switchboard as they are successively initiated. In the illustrated arrangement, distributor relays are only shown for three positions of the switchboard, but it will be understood that in the equipment as installed, the distributor 13 includes one distributor relay for each of the eight positions provided at this switchboard. The manner in which the additional five relays may be wired into the distributor circuit will be readily apparent from the foregoing explanation.

It will also be apparent from this explanation that if any position is busy at the time its turn for allotment occurs in the allotting chain, the position will be passed over and the next succeeding idle position will be selected to receive the next call. Thus if the second position is busy but the third position is idle at a time when the allotted first position receives a call, the guard lead C3926 extending to the busy second position of the switchboard is marked with ground potential. Accordingly, when the second distributor relay R3920 operates to release the first distributor relay R3910, a circuit is completed through the contacts 3925 and 3914 for energizing the third distributor relay R3930. This relay, in operating, opens its contacts 3934 to release the second distributor relay R3920 corresponding to the busy second position of the switchboard, and locks up through its contacts 3935 and the winding of the reset relay R3900. Under the conditions assumed, the third position is not busy so that the guard conductor C3928 individual to that position is not connected to ground. Accordingly, no circuit is provided for reoperating the first distributor relay R3910, and the third distributor relay R3930 remains in its operated position to allot the third position of the switchboard to receive the next call. In a similar manner any one of the other positions may be passed over in the allotting sequence determined by the distributor relays if the position is occupied with a call at the time its turn for allotment occurs.

If all positions of the switchboard 11 become busy at the same time, or all of the links at all of the positions are concurrently occupied with calls, the distributor start lead C3963 is disconnected from ground. Thus during each interval when the position circuit 18 of the No. 1 position

- is occupied with a call, the start relay R3310 is deenergized to open the path through its contacts 3314 for impressing ground potential upon this start lead. The remaining paths individual to the other position circuits are similarly opened during those intervals when the associated position circuits are occupied with calls. Accordingly when an all-busy condition prevails, the indicated start lead is disconnected from ground. 5 Should this occur, the reset relay R3900 and any operated one of the distributor relays are deenergized and restore. In releasing, the reset relay R3900 closes its contacts 3901 to reprepare the start circuit for the first distributor relay R3910. With all of the distributor relays deenergized the operating circuit for the start relay R2740 of the common start circuit 12 is held open at the contacts 3911, 3921, 3931, etc., so that operation of the common start circuit is suspended. 10 15 20 25 30 35
- When the all-busy condition of the operator positions at the switchboard 11 is terminated, ground potential is again applied to the distributor start lead C3963 in the position circuit individual to the position that has been released for use. When this occurs, the first distributor relay R3910 and the reset relay R3900 are reoperated in the order named. In operating, the relay R3900 opens its contacts 3901 to interrupt the start circuit to the first distributor relay R3910. The latter relay, upon operating, initiates the sequential operation of the succeeding distributor relays until such time as the relay corresponding to the position that has been released, is operated. Thus the idle position is selected to receive the next call.

OPERATION OF THE COMMON START CIRCUIT 12

- In considering the operation of the common start circuit 12, it will be understood that calls 40 of different types may be routed to the toll operator switchboard 11 over a number of different routes. For example, a call incoming from the toll office No. 1 may be routed to the toll operator switchboard 11 in the central office 10 over a path which includes the trunk 5, the trunk circuit 26, the finder 36 and the selector 37 of the link 35, the toll selector 32 and the inward trunk circuit 25. Alternatively, this call may be extended to 45 the toll operator and switchboard 11 from the toll selector 32 through the interposition trunk circuit 24. Inward toll calls may also be routed to the toll operator switchboard 11 from the toll office No. 2, or the manual office No. 2. C. L. R. 50 55 60 65 70 calls originating in the central office area may also be extended to the toll operator switchboard 11 from lines of different types through the local automatic switching equipment of the central office. For example, a call originating at the sub-station A on the private line 44 may be extended to the toll operator switchboard 11 through the automatic switch train 33 and the C. L. R. trunk circuit 23. Outgoing toll calls originating in the central office area may also be extended to the toll operator switchboard 11 from lines of the paystation type, in which case the coin control facilities of the switchboard must be used to assess the proper charges. In the common start circuit 12, calls of the last-mentioned type, i. e., those originating on paystation lines, are included in the same class as C. L. R. calls originating on private lines.

The common start circuit 12 is arranged to clear out the calls awaiting answering at the switchboard 11 in a particular order determined by the

level termination of the trunk circuits in the banks of the various answer switches. This circuit is also so arranged that C. L. R. and inward toll calls are handled in rotation. More specifically, the arrangement is such that both the C. L. R. and the toll calls are locked up in batches for distribution to the different operator positions of the switchboard 11, and no subsequently initiated calls will be included in the distribution sequence until each batch of calls is released from the common start circuit 12 to the switchboard.

To consider this arrangement in somewhat more detail, it may be assumed that the start relay R2740 is energized in series with the position start relay R3210, and that calls are present before the second and ninth levels of the answer switches associated with the several operator positions. From the illustrated trunking arrangement it will be understood that the calls appearing before the second levels of the answering switches are of the C. L. R. type and that the calls appearing before the ninth levels of the answer switches are of the inward toll type. When calls appear before the second contact levels of the answer switches, the start lead C2852 individual to this level and extending to the C. L. R. trunk circuits terminating in this particular level is connected to ground in the trunk circuits occupied with the calls. Similarly, the ninth start lead C2859 is connected to ground in the inward trunk circuits occupied with the inward toll calls. When the start lead C2852 is connected to ground, the C. L. R. level relay R2820 is energized through the contacts 2817 and locks to the grounded lead C2852 through its contacts 2822. Similarly, when ground potential is applied to the ninth start lead C2859, the ninth level relay R2890 is energized through the contacts 2812 and locks to the grounded lead C2859 through its contacts 2892.

The level relay R2820, upon operating, also closes its contacts 2821 to energize the C. L. R. lockout relay R2815. At its contacts 2823, the relay R2820 closes an obvious circuit for energizing the C. L. R. relay R2760. At its contacts 2824, the relay R2820 prepares a path for impressing ground potential upon the level marking lead C2842 which extends to the second contact in the level marking contact set 2410 of the answer switch 16 and to the corresponding contacts of the level marking contact sets in the other answer switches.

The C. L. R. lockout relay R2815, upon operating, opens its contacts 2817 to interrupt the operating circuit for the second level relay R2820. At its contacts 2816, the relay R2815 opens a point in the operating circuit for the third level relay R2830. The lockout relay R2815 is also provided with two additional sets of break contacts, through which the operating circuits for the fourth and fifth level relays, not shown, extend. It will be understood, therefore, that following the operation of the second level relay R2820 and the C. L. R. lockout relay R2815, the third, fourth and fifth level relays cannot be energized in response to the application of ground potential to the third, fourth and fifth level marking leads which extend to the various C. L. R. trunk circuits. Thus calls routed to these trunk circuits cannot be distributed to the switchboard 11 until such time as the calls appearing before the second levels of the answer switches have all been routed to the switchboard and the two relays R2820 and R2815 are released in the manner explained below.

The C. L. R. relay R2760, upon operating, closes its contacts 2761 to complete an obvious circuit

for energizing the relay R2730. At its contacts 2763, the relay R2760 prepares a path for impressing ground potential upon any one of the second to fifth level marking leads, including the illustrated second and third marking leads C2842 and C2843. At its contacts 2765, the relay R2760 completes the prepared circuit for energizing the start relay R2740 in series with the position start relay R3210 of the selected No. 1 operator position. At its contacts 2766, the relay R2760 connects the signal lead C2745 to ground, thereby to energize the C. L. R. signal lamps 4121 as provided at the different positions of the switchboard 11.

The ninth level relay R2890, upon operating, closes its contacts 2891 to energize the toll lockout relay R2810. At its contacts 2893, the relay R2890 completes an obvious circuit for energizing the toll relay R2750. At its contacts 2894, the relay R2890 prepares a path for impressing ground potential upon the ninth level marking lead C2849.

The toll lockout relay R2810, upon operating, opens its contacts 2812 to interrupt the operating circuit for the ninth level marking relay R2890. At its contacts 2811, the relay R2810 opens a point in the operating circuit for the tenth level relay R2800. This lockout relay is also provided with three additional sets of break contacts through which the operating circuits for the sixth to eighth level relays, not shown, extend. It will be understood, therefore, that with the lockout relay R2810 operated, subsequently initiated calls appearing before the sixth, seventh, eighth and tenth levels of the answer switches are prevented from being distributed to the switchboard 11 until after all of the calls appearing before the ninth levels of the answering switches have been extended to the switchboard for answering.

The toll relay R2750, upon operating, closes its contacts 2751 to complete an obvious multiple circuit for energizing the relay R2730. At its contacts 2752, the relay R2750 prepares a path for impressing ground potential upon the sixth to tenth level marking leads. At its contacts 2755 the relay R2750 completes an obvious multiple circuit for energizing the start relay R2740 in series with the position start relay R3210. At its contacts 2756, the relay R2750 connects the signal lead C2744 to ground, thereby to energize the toll signal lamps 4122 as provided at the different positions of the switchboard 11.

The relay R2730, upon operating, closes its contacts 2731 to prepare a circuit for energizing the lower winding of the change call relay R2710. When the start relay R2740 is energized in series with the position start relay R3210, it locks to ground through its contacts 2742, and closes its contacts 2741 to complete circuits through the contacts 2712 and 2721 for energizing the lower winding of the relay R2710 and both windings of the relay R2720. The change call relay R2720 is differentially wound so that when its two windings are concurrently energized it remains in its restored position. The other change call relay R2710 is also differentially wound. Accordingly, this relay operates when only its lower winding is energized. In operating, the relay R2710 locks to ground through its contacts 2711. At these contacts the relay R2710 also completes an alternative circuit through the contacts 2731 for maintaining the upper winding of the relay R2720 energized. After completing this alternative circuit the relay R2710 opens its contacts 2712 to interrupt the initially completed circuit for energizing the upper winding of the relay R2720.

When the position start relay R3210 of the

operator position circuit 18 is energized in series with the start relay R2740 of the common start circuit 12, it functions in the manner explained below to cause the answer switch of a link selected by the link distributor 19 to search for the C. L. R. call which is marked in the lowest numbered rotary positions of the respective second contact levels in the different answer switches. In this regard it may be assumed that the illustrated link 15, including the answer switch 16, has been selected by the link distributor 19 to extend the call to the operator position circuit 18. The vertical movement of this answer switch is determined by the marking with ground potential of one of the ten level marking leads terminating at the contacts of the contact set 2410. In this regard it will be noted that, with the relays R2820, R2760 and R2750 operated, and the change call relay R2720 restored in the common start circuit 12, the second level marking lead C2842 is marked with ground potential over a path which includes the contacts 2824, 2724 and 2763. Accordingly, when the wipers of the answer switch 16 are operated to a position opposite the second level of contacts in the associated contact bank, vertical movement of these wipers is arrested and rotary movement thereof is initiated. When these wipers are operated in the rotary direction to select the first trunk circuit occupied with a C. L. R. call, the rotary movement thereof is arrested and the call is extended to the position circuit 18 in the manner explained below. Incident to the extension of the call to the position circuit 18, the circuit for energizing the position start relay R3210 in series with the start relay R2740 of the common start circuit 12 is broken, and the operating circuit for the start relay R3310 is opened, causing all three of these relays to restore. Incident to the release of the start relay R3310, the position distributor 13 operates to select another idle position of the switchboard 11 to receive the next call in the manner explained above. When an idle position is selected by the distributor 13, the start relay R2740 of the common start circuit 12 is energized in series with the position start relay individual to the selected position and reoperates.

Upon restoring, the start relay R2740 opens its contacts 2742 to interrupt its locking circuit, and at its contacts 2741 deenergizes the lower winding of the change call relay R2720. When its lower winding is thus deenergized, the relay R2720 operates and opens its contacts 2724 to disconnect the second level marking lead C2842 from ground. Thus the calls appearing before the second contact levels in the banks of the answer switches are no longer marked in the level marking contact sets of these switches. The relay R2720, in opening its contacts 2724, also interrupts the incomplete paths for impressing ground potential upon the third, fourth and fifth level marking leads. At its contacts 2723, the relay R2720 prepares the common portion of the paths for impressing ground potential upon the sixth to tenth level marking leads, and in so doing applies ground potential to the ninth marking lead 2849 through the contacts 2894 of the operated ninth level relay R2890. Thus an indication is provided to the answer switches associated with the operator switchboard 11 that certain of the trunk circuits having terminations in the ninth contact levels thereof are occupied with calls. At its contacts 2721, the relay R2720 opens another point in the circuit for energizing its own lower winding. At its contacts 2722, the

relay R2720 prepares a circuit for energizing the upper winding of the change call relay R2710.

When the start relay R2740 reoperates in response to the operation of the position distributor 13 to select another operator position to receive the next call, it closes its contacts 2741 to energize the upper winding of the relay R2710 through the contacts 2722. When both windings of the relay R2710 are thus concurrently energized the relay R2710 restores. In releasing, this relay first closes its contacts 2712 to complete a circuit through the contacts 2741 for energizing the upper winding of the relay R2720 in parallel with its own lower winding, and then opens its contacts 2711 to interrupt the alternative circuit for energizing these two parallel connected windings.

As indicated above, with the change call relay R2720 operated, the second level marking lead C2842 is disconnected from ground while the ninth level marking lead C2849 is connected to ground through the contacts 2894, 2723 and 2752. Accordingly, the answer switch of the link assigned to extend the call to the selected position of the operator switchboard is permitted to pass the second contact level of its bank during the vertical movement thereof and is only stopped when it selects the ninth contact level in its contact field, i. e., the contact level in which the unanswered toll calls are waiting. After one of these calls is extended to the switchboard 11 through the assigned link, the start relay R2740 is momentarily deenergized during the operation of the position distributor 13 to select another idle operator position, after which it is energized in series with the position start relay associated with the selected idle position. In releasing, the start relay R2740 opens its contacts 2741 to deenergize the two windings of the relay R2710 and the upper winding of the relay R2720. Both of the change call relays R2710 and R2720 are thus caused to release. When the start relay R2740 subsequently reoperates in response to the operation of the distributor 13 to select an idle operator position to receive the next call, it again energizes both windings of the relay R2720 and the lower winding of the relay R2710 in the manner previously explained. Thus the relay R2710 is reoperated while the relay R2720 remains in its restored position. It will be understood from the preceding explanation that with the relay R2720 in its released position, the ninth level marking lead C2849 is disconnected from ground while the second level marking lead C2842 is connected to ground through the contacts 2824, 2724 and 2763. From this point on, the manner in which the two change call relays R2710 and R2720 are controlled by the start relay R2740 to cause the toll and C. L. R. calls alternately to be distributed to the toll operator switchboard 11 is exactly the same as explained above.

When all of the C. L. R. calls appearing before the second contact levels of the answer switches have been extended to the toll operator switchboard 11, the start lead C2852 is disconnected from ground in the various C. L. R. trunk circuits occupied with the calls. In this regard it will be understood that each trunk circuit appearing before the second contact levels of the answer switches is provided with a path for impressing ground potential upon the start lead C2852 when a call is routed to the trunk circuit, and that this path is broken in the trunk circuit incident to the operation of one of the answer switches to seize the trunk circuit. Accordingly, when all of the

C. L. R. calls appearing before the second contact levels of the answer switches have been extended to the operator switchboard 11, all of the multiple paths for impressing ground potential upon the start lead C2852 are broken to deenergize the second level relay R2820. This relay, in releasing, opens its contacts 2824 further to interrupt the path for impressing ground potential upon the second level marking lead 2842. At its contacts 2823, the relay R2820 opens the operating circuit for the C. L. R. relay R2760. At its contacts 2821, the relay R2820 deenergizes the lockout relay R2815. The C. L. R. relay R2760, upon restoring, opens its contacts 2761 to interrupt the multiple circuit for energizing the relay R2730, the latter relay being held energized through the make contacts 2751 of the toll relay R2750 so long as any unanswered inward toll calls are present before the ninth contact levels of the answer switches. At its contacts 2763, the relay R2760 opens a point in the common portion of the paths for impressing ground potential upon the second, third, fourth and fifth level marking leads. At its contacts 2765, the relay R2760 opens a multiple point in the available circuits for energizing the start relay R2740. At its contacts 2766, the relay R2760 disconnects the signal lead C2745 from ground, thereby to deenergize the C. L. R. signal lamps 4121 as provided at the different positions of the switchboard 11.

If calls are present in any of the C. L. R. trunk circuits appearing before the third, fourth and fifth contact levels of the answer switches at the time the C. L. R. lockout relay R2815 releases, the C. L. R. level relays corresponding to the contact levels before which the calls appear are operated and locked up. Thus if one of the trunk circuits appearing before the third contact levels of the answer switches is occupied with a call, the start lead C2853 is connected to ground therein so that a circuit is completed through the contacts 2816 for energizing the third level relay R2830 when the C. L. R. lockout relay R2815 restores. In a similar manner the fourth and fifth level relays may be energized in response to the release C. L. R. lockout relay R2815, providing calls have been extended to the trunk circuits appearing before the fourth and fifth contact levels of the answer switches. These level relays, in operating, lock to their respective associated marking leads and close multiple circuits for energizing the C. L. R. relay R2760 and the C. L. R. lockout relay R2815. Thus the third level relay R2830, in operating, locks through its contacts 2832 to the marking lead C2853, and closes its contacts 2831 and 2833 to complete circuits for energizing the relays R2815 and R2760, respectively. In operating, the level relays also prepare the marking paths to their respective associated level marking leads. Thus the third level relay R2830 closes its contacts 2834 to prepare a path for impressing ground potential upon the third level marking lead C2843. The C. L. R. lockout relay R2815, in operating, opens its break contacts to interrupt the operating circuits for the non-operated ones of the second, third, fourth and fifth level relays. Thus, at its contacts 2817, for example, the relay R2815 opens the operating circuit for the second level relay R2820 to prevent this relay from being energized in response to the extension of a call to a C. L. R. trunk circuit appearing before the second contact levels of the answer switches. It will be understood, therefore, that after the C. L. R. lockout relay R2815 operates, a new batch of C. L. R. calls

is effectively stored in the common start circuit 12, and that these calls must be disposed of before the level relays can be reset to include subsequently initiated calls appearing before those contact levels of the answer switches which correspond to non-operated ones of the C. L. R. level relays. It will also be understood that with two or more of the third, fourth and fifth level relays in the common start circuit 12 operated, the calls appearing before the third contact levels of the answer switches will be extended to the toll operator switchboard 11 before the calls appearing before the fourth and fifth contact levels of these switches are reached. Thus with the third, fourth and fifth level relays operated, ground potential is applied to the third, fourth and fifth level marking leads through the contacts 2763 and 2724 each time the change call relay R2720 releases. Any answer switch, however, in searching for a marked level will stop its vertical movement when the first marked level is reached. Thus, in the case assumed, the answer switch 18, for example, will, during its vertical movement, find the marked lead C2843 at the end of its third vertical step and cannot be operated beyond this step to reach the marked fourth and fifth level marking leads. When, however, all calls appearing before the third contact levels of the answer switches are extended to the toll operator switchboard 11, the third level relay R2830 is released in the manner explained above and opens its contacts 2834 to prevent ground potential from being applied to the third level marking lead C2843. Accordingly, the answer switches assigned to extend the C. L. R. calls to the toll operator switchboard are now controlled over the fourth level marking lead until all of the calls appearing before the fourth contact levels of the answer switches have been extended to the switchboard 11. After these calls are disposed of, the fourth level relay releases to permit the answer switches to be controlled over the fifth level marking lead, whereby the calls appearing before the fifth contact levels of the answer switches can be extended to the toll operator switchboard. It will also be understood from the above explanation that as each batch of calls stored in the common start circuit 12 is disposed of, the C. L. R. lockout relay R2815 is released to permit waiting C. L. R. calls to be marked in the common start circuit.

When all of the inward toll calls appearing before the ninth contact levels of the answer switches are extended to the switchboard 11, the marking lead C2859 is disconnected from ground in the trunk circuits occupied with these calls. The ninth level relay R2890 is thus deenergized and opens its contacts 2891 to deenergize the toll lockout relay R2810. At its contacts 2893, the relay R2890 opens the operating circuit for the toll relay R2750. At its contacts 2894, the relay R2890 opens the path for connecting the ninth level marking lead C2849 to ground in the common start circuit 12. The toll relay R2750, in releasing, opens its contacts 2751 to interrupt the multiple operating circuit for the relay R2730, but the latter relay is held energized through the contacts 2761 so long as the C. L. R. relay R2760 is operated. At its contacts 2752, the relay R2750 opens a point in the common portion of the paths for connecting the sixth to tenth level marking leads to ground in the common start circuit 12. At its contacts 2755, the relay R2750 opens one of the multiple circuits for energizing the start relay R2740. At its contacts 2756, the relay

R2750 disconnects the signal lead C2744 from ground, thereby to deenergize the toll signal lamps 4122 as provided at the several positions of the switchboard 11.

If inward toll calls are waiting in the inward trunk circuits appearing before the sixth, seventh, eighth and tenth contact levels of the answer switches at the time the toll lockout relay R2810 releases, the level relays corresponding to these different contact levels of the answer switches are energized. For example, if one of the inward trunk circuits appearing before the tenth contact levels of the answer switches is occupied with a call, the marking lead C2850 is connected to ground in that trunk circuit. Accordingly, the tenth level relay R2800 is energized through the contacts 2811 when the toll lockout relay R2810 restores. In operating, the energized level relays lock to their respective corresponding marking leads, close multiple operating circuits for the toll lockout relay R2810, close multiple circuits for the toll relay R2750, and prepare the respective corresponding level marking paths. For example, the tenth level relay R2800, upon operating, locks to the grounded marking lead C2850 through its contacts 2802; closes its contacts 2801 to energize the toll lockout relay R2810; closes its contacts 2803 to energize the toll relay R2750; and closes its contacts 2804 to prepare the path for connecting the tenth level marking lead R2840 to ground in the common start circuit 12.

After a new batch of inward toll calls is thus stored in the common start circuit 12, subsequently initiated calls appearing before the contact levels of the answer switches which correspond to non-operated level relays in the common start circuit are effectively locked out. Thus when the toll lockout relay R2810 operates, it opens the operating circuits for the five associated level relays at its contacts 2811, 2812, etc. It will be understood from the foregoing explanation that the inward toll calls marked in the common start circuit 12 are routed to the toll operator switchboard 11 in the order in which they appear before the different contact levels of the answer switches. Thus if the sixth level relay is operated, all calls appearing before the sixth contact levels of the answer switches must be extended to the toll operator switchboard 11 before the answer switches can obtain access to the calls appearing before the seventh contact levels thereof. This order of call handling, it will be recalled, results from the manner in which the level marking leads are connected to the contacts of the level marking contact sets respectively provided in the different answer switches.

ROUTING A CALL TO THE FIRST POSITION OF THE SWITCHBOARD 11

In considering the manner in which calls are extended to the toll operator switchboard 11, it may be assumed that a call originating on the line 44 has been extended through the automatic switch train 33 to the C. L. R. trunk circuit 23 and has been marked in the common start circuit 12 in the manner just explained. It may be assumed further that the No. 1 operator position is assigned by the position distributor 13 to receive the call and that the link distributor 19 has selected the link 15 for use in extending the call from the trunk circuit 23 to the operator position circuit 18. In this regard it will be recalled that with the position circuit 18 idle but conditioned for use, the three relays R2910,

Immediately the operator position distributor 13 selects the No. 1 position to handle the call, the previously mentioned circuit is completed for energizing the position start relay R3210 in series with the start relay R2740 of the common start circuit 12. This circuit may now be traced as extending from ground by way of the contacts 2765, the winding of R2740, the start lead C2743, the contacts 3911, C3961, the contacts 3311 and 3254, C4131, the contacts 3032, and the winding of R3210 to battery. In operating, the relay R3210 closes its contacts 3213 to prepare circuits for energizing the sender start relay R3430 and the link start relay R2530. At its contacts 3212, the relay R3210 completes a circuit through the contacts 3831 for energizing the relay R3040. At its contacts 3211, the relay R3210 completes the prepared operating circuit for the connect relay R2630, this circuit extending from ground by way of the contacts 2911, 3015, 3051, 3106 and 3211, C3214, the contacts 3801 and 3811, C3841, the vertical off-normal springs 2504, the contacts 2511 and 2626, and the upper winding of R2630 to battery.

In operating, the call lock relay R3040 locks to ground through the contacts 3031 and 3043, and closes its contacts 3044 to complete an obvious shunt across the contacts 3021 as included in the circuit for energizing the start relay R3310. At its contacts 3042, the relay R3040 prepares a circuit for energizing the switching relay R3010 and the lower winding of the connect relay R2630 in series. At its contacts 3041, the relay R3040 prepares a circuit for energizing the relay R3230 as provided at the next adjacent operator position, i. e., the position to which calls are transferred when the illustrated No. 1 position is not attended.

The connect relay R2630, upon operating, locks up in a circuit which includes its lower winding, the contacts 2631, C2576, the contacts 3042 and 3102', and the winding of the switching relay R3010. At its contacts 2632, the relay R2630 prepares a circuit for energizing the start sending relay R2650. At its contacts 2633, the relay R2630 completes an obvious circuit for energizing the connect relay R2560. At its contacts 2634, the relay R2630 connects the link busy lamp 2604 to be energized in accordance with the ground pulses transmitted over the 60 I. P. M. interrupter lead C2638. At its contacts 2635, the relay R2630 opens an incomplete alternative circuit for steadily energizing the busy lamp 2604. At its contacts 2636, the relay R2630 prepares an alternative circuit for energizing the call lock relay R3040.

The connect relay R2560, upon operating, closes its contacts 2561 and 2564 to connect the talking leads extending to the front of the link 15 to the terminals of the repeating coil 2906 over paths which include the front talking leads C2572 and C2574, the contacts 3151 and 3154, the contacts 3111, the contacts 3101 and 3103, and the contacts 3011 and 3013. At its contacts 2562 and 2565, the relay R2560 connects the talking leads extending to the rear of the link 15 to the terminals of the repeating coil 2906 over paths which respectively include the rear talking leads C2573 and C2575, the contacts 3201 and 3204, the contacts 3111, the contacts 3101 and 3103, and the contacts 3011 and 3013. At its contacts 2563 and 2566, the relay R2560 disconnects the talking leads extending to the rear of the link from the talking leads extending to the front of the link. At its contacts 2568, the relay R2560 prepares a circuit for energizing the blocked sender relay

R2610. At its contacts 2567, the relay R2560 prepares a path for short-circuiting the upper winding of the cut-through relay R2620. At its contacts 2569, the relay R2560 prepares a circuit for energizing the sender seize relay R3250. At its contacts 2561', the relay R2560 completes the prepared operating circuit for the start relay R2530, this circuit extending from ground by way of the contacts 3213, 3222 and 3254, the start lead C2580, the contacts 2561', and the winding of R2530 to 10 battery.

The switching relay R3010, upon operating in the position circuit 18, opens its contacts 3011 and 3013 to disconnect the front and rear talking leads C2512, C2513, C2574 and C2575 from the windings of the repeating coil 2906, and closes its contacts 3012 and 3014 to connect these talking leads to the line terminals of the hybrid coil 2905. At its contacts 3015, the relay R3010 disconnects the lead C2566 from ground in the position circuit 18, and opens the distributor controlled operating circuit for the connect relay R2630. This connect relay, however, remains energized in series with the switching relay R3010. At its contacts 3016, the relay R3010 completes a circuit through the contacts 2911 for energizing the slow-to-release relay R3050. In operating, the latter relay opens its contacts 3051 further to interrupt the distributor controlled operating circuits for the connect relays of the links associated with the No. 1 position of the switchboard.

The start relay R2530, upon operating, opens its contacts 2531 to interrupt the path over which the terminating impedance, comprising the condenser 2517 and the resistor 2518, is normally bridged across the talking conductors extending to the rear of the link. At its contacts 2532, the relay R2530 prepares a circuit for energizing the front supervisory signal lamp 2516. At its contacts 2533, the relay R2530 prepares the operating circuit for the front supervisory relay R2600. At its contacts 2534, the relay R2530 opens an incomplete alternative circuit for energizing the front supervisory lamp 2516. At its contacts 2535, the relay R2530 opens a point in the operating circuit for the release rear relay R2510. At its contacts 2536, the relay R2530 completes an obvious circuit for energizing the upper winding of the supervisory relay R2520. At its contacts 2538, the relay R2530 completes a circuit through the contacts 2432, 2452, 2449, 2461', 2471 and 2485 for energizing the vertical magnet 2411 of the Strowger switching mechanism. At its contacts 2539, the relay R2530 prepares a circuit for energizing the rear supervisory signal lamp 2603. At its contacts 2531', the relay R2530 prepares a circuit for energizing the rear supervisory relay R3260. At its contacts 2532', the relay R2530 opens an incomplete alternative circuit for energizing the rear supervisory lamp 2603. The relay R2520, in operating, opens its contacts 2521 which are included in certain of the available circuits for controlling the rear supervisory lamp 2603. At its contacts 2522, the relay R2520 opens a point in the path for short-circuiting its own lower winding.

The vertical magnet 2411, upon operating elevates the wipers 2401 to 2409, inclusive, one step wherein they are positioned opposite the first level of contacts in the associated contact field. At its contacts 2411a, the magnet 2411 closes an obvious circuit for energizing the stepping relay R2470. When thus energized the relay R2470 opens its contacts 2471 to deenergize the vertical magnet 2411. This magnet now restores and

opens its contacts 2411a to deenergize the stepping relay R2470. The relay R2470 now restores and recloses its contacts 2471 to recomplete the circuit for energizing the vertical magnet. The 5 interrelated operation of the stepping relay R2470 and the vertical magnet 2411 continues until the wipers 2401 to 2409, inclusive, are elevated to a position opposite the level of bank contacts before which the calling C. L. R. trunk circuit 23 appears. In this regard it will be understood that the wipers 2401 to 2409, inclusive, are operated one step in the vertical direction each time the vertical magnet 2411 is energized.

Incident to the vertical off-normal movement 15 of the enumerated wipers, the off-normal springs 2414 are moved into engagement to prepare a circuit for energizing the lower winding of the change-over relay R2480; the vertical off-normal springs 2504 are disengaged to open another point in the operating circuit for the connect relay R2630; the off-normal springs 2502 are engaged to prepare the operating circuit for the release magnet 2501; and the off-normal springs 2503 are moved into engagement to prepare the 20 operating circuit for the release rear relay R2510.

If the trunk circuit 23 is terminated by means of the trunk 23d at a contact set in the third contact level, the third level marking lead extending between the common start circuit 12 and the level marking contact set 2410 is connected to ground in the common start circuit. Accordingly, when the wiper 2409 is positioned to engage its associated third contact, the relays R2470 and R2480 are energized in series 30 over a circuit which extends from ground by way of the contacts 2763, 2724 and 2834, the third level marking lead C2843, the wiper 2409, the upper winding of R2480, the contacts 2515 and 2488, and the winding of R2470 to battery. When 35 energized in this circuit the stepping relay R2470 remains operated to prevent further energization of the vertical magnet 2411. Thus vertical movement of the wipers 2401 to 2409, inclusive, is arrested.

45 The change-over relay R2480 operates when its upper winding is energized in series with the stepping relay R2470 over the above-traced test circuit. In operating, this relay first closes its primary make contacts 2487 to complete a locking circuit for itself, this circuit extending from ground by way of the off-normal springs 2414, the lower winding of R2480, the contacts 2487, and the resistor 2489 to battery. After this circuit is completed the relay R2480 opens its contacts 2488 to interrupt the above traced test circuit and thus deenergize the stepping relay R2470. At its contacts 2485, the relay R2480 opens another point in the above-traced operating circuit for the vertical magnet 2411. At its 50 contacts 2486, the relay R2480 prepares the operating circuit for the rotary magnet 2412. At its contacts 2484, the relay R2480 prepares the operating circuits for the two test relays R2430 and R2450 and also prepares a path for impressing ground potential upon the test wipers 2405 and 2406. At its contacts 2483, the relay R2480 opens a point in the incomplete operating circuit for the release rear relay R2510. At its contacts 2481, the relay R2480 disconnects the all-links-busy lead C3045 from ground in the link 15, this lead normally being connected to ground over a path which includes the contacts 2512, 2444, 2464, 2481 and 2627. Similar paths for impressing ground potential upon the lead 55 C3045 are provided in each of the other links

60 70 75

associated with the No. 1 operator position, so that the all-links-busy relay R3020 is prevented from releasing until all of these links are occupied with calls. At its contacts 2482, the relay R2480 completes a circuit for energizing the tone relay R3110 of the operator position circuit 18, this circuit extending from ground by way of the contacts 2512, 2444, 2464 and 2492, C2567, the contacts 3344 and 3133, and the winding of R3110 to battery.

When thus energized the slow-to-release tone relay R3110 closes its contacts 3112 and 3113 to complete a circuit for transmitting dial tone signal current through the receiver 2901 of the operator headset. The circuit traversed by this current extends from the high potential side of the dial tone generator, not shown, by way of the dial tone lead C3144, the contacts 3122, 3112, 3101 and 3012, the upper windings of the hybrid coil 2905, and the contacts 3014, 3103 and 3113, to the grounded side of the dial tone generator. When this circuit is completed dial tone current is transmitted through the hybrid coil 2905 to the receiver 2901 and is reproduced as the usual dial tone signal. In operating, the relay R3110 also locks up in a circuit including the contacts 3115 and 3133. At its contacts 3114, the relay R3110 closes an obvious circuit for energizing the slow-to-operate tone relay R3120. The latter relay, in operating, closes its contacts 3121 to prepare an alternative circuit for transmitting the dial tone current through the upper windings of the hybrid coil 2905, and then opens its contacts 3122 to interrupt the above-traced circuit traversed by this current. At its contacts 3123, the relay R3120 closes an obvious circuit for energizing the slow-to-operate tone relay R3130. The latter relay, upon operating, closes its contacts 3131 to complete the alternative circuit for transmitting dial tone current through the upper windings of the hybrid coil 2905, and locks to ground through the contacts 3132 and 3115. This relay also locks to the grounded lead C2567. At its contacts 3133, the relay R3130 deenergizes the relay R3110. The latter relay restores after an interval measured by its release period, and opens its contacts 3112 and 3113 to interrupt the alternative circuit traversed by the dial tone signal current. At its contacts 3111, the relay R3110 reconnects the talking leads C2514 and C2515 to the talking leads C2562 and the right upper terminal of the hybrid coil 2905. At its contacts 3114, the relay R3110 deenergizes the relay R3120. At its contacts 3115, the relay R3110 opens another point in its own locking circuit and one of the established locking circuits for the tone relay R3130. The latter relay remains in its operated position until such time as the lead C2567 is disconnected from ground in the link 15 or the relay R3340 operates. From the above explanation it will be understood that the three tone relays R3110, R3120 and R3130 cooperate to transmit two short splashes of dial tone signal current through the receiver 2901 of the operator headset, so that a zip-zip signal is reproduced by this receiver to inform the operator attending the No. 1 position of the switchboard that a call is being routed to her position for answering.

As indicated above, the stepping relay R2470 is deenergized in response to the operation of the change-over relay R2480. In releasing, the stepping relay closes the prepared operating circuit for the rotary magnet 2412, this circuit extending from ground by way of the contacts 2538

2432, 2452, 2449, 2461', 2471 and 2468, and the winding of the magnet 2412 to battery. When thus energized, the magnet 2412 operates to rotate the wipers 2401 to 2408, inclusive, one step, 5 wherein they are positioned to engage the contacts forming the first contact set of the selected third level. In operating, the magnet 2412 also closes its contacts 2412a to energize the stepping relay R2470. The relay R2470 now opens its contacts 2471 to deenergize the rotary magnet 2412. In releasing, this magnet opens its contacts 2412a to deenergize the stepping relay. This relay, upon restoring, recloses its contacts 2471 to again energize the rotary magnet. The interrelated operation of the relay R2470 and the rotary magnet 2412 continues until the wipers 2401 to 2408, inclusive, are positioned to engage the contacts at which the conductors of the trunk 23d are terminated.

In this regard it will be recalled that the answer switch 16 is of the 200 line type, being provided with duplicate sets of line wipers, duplicate test wipers 2405 and 2406, each individual to a group of 100 lines of trunks, and duplicate extra control wipers 2407 and 2408, also individual to the two groups of 100 lines. In the illustrated wiring arrangement the trunk 23d is included in the first 100 line group so that the test wiper 2405 is utilized in locating the rotary position of the contact set in the third contact level at which the conductors of this line are terminated. More specifically, when this wiper is operated to engage the contact terminating the test conductor 23c of the line 23d, a circuit is completed for energizing the test relay R2430 in series with the cut-off relay, not shown, of the trunk circuit 23. This circuit extends from ground by way of the contacts 2484 and 2466, the winding of R2430, the contacts 2448, the test wiper 2405, the test conductor 23c, and the winding of the cut-off relay embodied in the trunk circuit 23 to battery. When thus energized the indicated cut-off relay operates to open the path provided therein for impressing ground potential upon the third start lead C2853, whereby the trunk circuit 23 is no longer marked as a calling trunk circuit in the common start circuit 12.

The test relay R2430 also operates when the above-described series test circuit is completed. 50 In operating, this relay closes its contacts 2431 to complete a circuit through the contacts 2538 for energizing the associated switching relay R2440. At its contacts 2432, the relay R2430 opens the above-traced operating circuit for the 55 rotary magnet 2412, whereby this magnet is deenergized and restores. In releasing, the magnet 2412 opens its contacts 2412a to deenergize the stepping relay R2470. This relay, upon restoring, closes its contacts 2471 to reprepare the operating circuit for the rotary magnet 2412.

The switching relay R2440, upon operating, locks to ground through the contacts 2445 and 2512. At its contacts 2444, the relay R2440 disconnects the lead C2567 from ground, thereby to deenergize the tone relay R3130. The release of the latter relay is without effect. At its contacts 2446, the relay R2440 opens a point in the circuit for energizing the test relay R2450 individual to the second group of 100 lines terminating in the contact field of the answer switch 16. At its contacts 2447, the relay R2440 completes a path through the lower winding of the relay R2520 and the contacts 2484 for impressing ground potential upon the test wiper 2405, thereby to provide a locking circuit for the cut-off relay of the

trunk circuit 23. At its contacts 2449, the relay R2440 opens another point in the common portion of the operating circuits for the vertical and rotary magnets 2411 and 2412, respectively. At its contacts 2448, the relay R2440 deenergizes the test relay R2430. At its contacts 2441', the relay R2440 completes a path through the normal post springs 2419 and the contacts 2538 for impressing ground potential upon the extra control wiper 2408. At its contacts 2442', the relay R2440 completes the prepared operating circuit for the relay R3250, this circuit extending from ground by way of the winding of R3250, the lead C2579, the contacts 2569, 2442' and 2487 and the resistor 2489 to battery. At its contacts 2443' the relay R2440 connects the link guard lead C3842 to ground, thereby to cause the link distributor 19 to select another idle link associated with the No. 1 position of the switchboard 11 in the manner previously explained. At its contacts 2443, the relay R2440 prepares an alternative operating circuit for the connect relay R2630. At its contacts 2441 and 2442, the relay R2440 completes the desired talking circuit between the calling substation A associated with the line 44 and the operator headset at the No. 1 position of the operator switchboard. This talking circuit as completed between the line wipers 2401 and 2402 of the Strowger switching mechanism in the answer switch 16 and the operator position circuit 18, includes the contacts 2441 and 2442, the contacts 2562 and 2565, the rear talking leads C2573 and C2575, the contacts 3201 and 3204, the contacts 3111, the contacts 3101 and 3103, the contacts 3012 and 3014, and the line windings of the hybrid coil 2905. After this talking circuit is completed the operator attending the No. 1 position of the switchboard may converse with the calling subscriber and ascertain the service desired.

As indicated above, the test relay R2430 is deenergized and restores in response to the operation of the switching relay R2440. In releasing, the indicated test relay opens its contacts 2431 to interrupt the operating circuit for the switching relay R2440, and closes its contacts 2432 to reprepare the operating circuits for the vertical magnet 2411 and the rotary magnet 2412.

Before considering the functions performed in response to the operation of the relay R3250, it is pointed out that if the calling trunk circuit appearing before the wipers of the answer switch 16 is terminated in the banks of this switch by a trunk, such, for example, as the trunk 25d, included in the second group of 100 lines, the test relay R2450 and the switching relay R2460 are utilized in lieu of the test relay R2430 and its associated switching relay R2440. Thus if the wipers 2401 to 2408, inclusive, are, during the rotary movement thereof, searching for the trunk 25d, the rotary test circuit is completed when the test wiper 2406 is operated to engage the contact terminating the test conductor 25c. In this case the test relay R2450 is energized in a circuit which extends from ground by way of the contacts 2484 and 2446, the winding of R2450, the contacts 2468, the wiper 2406, the test conductor 25c, and the winding of the cut-off relay provided in the inward trunk circuit 25 to battery. When thus energized, the relay R2450 opens its contacts 2452 to deenergize the rotary magnet 2412, whereby this magnet and the stepping relay R2470 are sequentially released. At its contacts 2451, the relay R2450 completes a circuit for energizing the switching relay R2460, this

circuit extending from ground by way of the contacts 2538, 2432 and 2451, and the winding of R2460 to battery.

When thus energized, the switching relay R2460 locks to ground through the contacts 2465 and 2512, and opens its contacts 2466 to interrupt the incomplete operating circuit for the test relay R2430. At its contacts 2464, the relay R2460 deenergizes the tone relay R3130. At its contacts 2467, the relay R2460 connects the test wiper 2406 to ground over a path including the lower winding of the relay R2520 and the contacts 2484, thereby to complete a circuit for energizing the cut-off relay of the trunk circuit 25 in series with the lower winding of the supervisory relay R2520. After completing this path the relay R2460 opens its contacts 2468 to deenergize the test relay R2450. The latter relay, in releasing, closes its contacts 2452 to reprepare the operating circuits for the vertical magnet 2411 and the rotary magnet 2412, and opens its contacts 2451 to interrupt the operating circuit for the switching relay R2460.

At its contacts 2469, the relay R2460 connects the extra control wiper 2407 to ground through the contacts 2538. At its contacts 2461', the relay R2460 opens a point in the operating circuits for the vertical magnet 2411 and the rotary magnet 2412. At its contacts 2462', the relay R2460 completes the previously traced operating circuit for the relay R3250 in the operator position circuit 18. At its contacts 2463', the relay R2460 connects the link guard lead C3842 to ground, thereby to cause the distributor 19 to select another idle link in the manner previously explained. At its contacts 2463, the relay R2460 prepares the above-mentioned alternative circuit for energizing the connect relay R2630. At its contacts 2461 and 2462, the relay R2460 connects the line wipers 2403 and 2404 to the talking leads C2573 and C2575, thereby to complete the desired talking circuit between the calling substation or operator position and the No. 1 position of the operator switchboard 11.

If during the rotary movement of the wipers 2401 to 2408, inclusive, the test wipers 2405 and 2406 are simultaneously operated to engage test contacts corresponding to calling trunk circuits in each of the two 100 line groups, preference is given to the calling line in the first 100 line group. This is accomplished by adjusting the relays R2430 and R2440, corresponding to the lines of the first group, to operate somewhat faster than the relays R2450 and R2460 corresponding to the relays of the second group. With this arrangement, the switching relay R2440 will be operated to deenergize the test relay R2450 before the latter relay can operate to energize its associated switching relay R2460. Because of this arrangement, the possibility of two calls being concurrently routed through the answer switch 16 to the operator position circuit 18 is precluded.

Seizing the sender control circuit 20 and the register sender 21

As pointed out in the foregoing explanation, the relay R3250 is energized and operates in response to the operation of either of the two switching relays R2440 and R2460. Upon operating, the relay R3250 closes its contacts 3251 to prepare a locking circuit for the relay R3340. At its contacts 3252, the relay R3250 connects the start lead C2580 to ground, thereby to provide a multiple circuit for energizing the start relay

R2530 of the answer switch 16. At its contacts 3254, the relay R3250 opens the initially completed circuit for energizing the start relay R2530. At its contacts 3253, the relay R3250 opens the previously traced operating circuit for the position start relay R3210. At its contacts 3256, the relay R3250 opens the previously traced operating circuit for the start relay R3310. At its contacts 3255, the relay R3250 completes the prepared operating circuit for the sender start relay R3430 of the sender control circuit 20, this circuit extending from ground by way of the contacts 2911, 3044, 3033, 3104', 3223, 3231, 3255, 3325, 3348 and 3402', and the winding of R3430 to battery. At its contacts 3257, the relay R3250 opens a point in the locking circuit for the accept call relay R2920.

The start relay R3310, upon restoring, opens its contacts 3311 further to interrupt the operating circuit for the position start relay R3210. At its contacts 3312, the relay R3310 opens another point in the locking circuit for the accept call relay R2920. At its contacts 3313, the relay R3310 connects the position guard lead C3962 to ground, thereby to mark the No. 1 position of the switchboard as busy in the position distributor 13. At its contacts 3314, the relay R3310 disconnects the distributor start lead C3963 from ground in the position circuit 18.

The position start relay R3210, upon restoring, opens its contacts 3213 further to interrupt the above-traced operating circuit for the link start relay R2530. At its contacts 3212, the relay R3210 opens the operating circuit for the relay R3040. At its contacts 3211, the relay R3210 disconnects the lead C3214 from ground in the position circuit 18, thereby to open the portion of the operating circuits for the connect relays of the various links associated with the No. 1 operator position.

The sender start relay R3430, upon operating, locks to ground through its contacts 3433 over a path which includes the contacts 3633', 3348, 3325, 3255, 3231, 3223, 3104', 3033, 3044 and 2911. At its contacts 3432, the relay R3430 closes an obvious circuit for energizing the connect relay R3400. At its contacts 3431, the relay R3430 prepares a circuit for energizing the sender connect relay R3700.

The relay R3400, upon operating, closes its contacts 3407 to prepare the operating circuit for the dial rear relay R3420. At its contacts 3408, the relay R3400 prepares locking circuits for the relays R3420, R3440 and R3520, and completes a circuit through the contacts 3412, 3431 and 3637 for energizing the sender connect relay R3700. At its contacts 3409, the relay R3400 completes a circuit for energizing the slow-to-release hold relay R3620, this circuit extending from ground by way of the contacts 3614, 3409 and 3413, and the winding of R3620 to battery. At its contacts 3401', the relay R3400 prepares a locking circuit for the error relay R3410. At its contacts 3402', the relay R3400 opens the above-traced operating circuit for the start relay R3430. At its contacts 3401 to 3406, inclusive, the relay R3400 operationally associates the control equipment of the link 15 and the position circuit 18 with the control equipment of the sender control circuit 20. More specifically, the relay R3400, in closing its contacts 3401 and 3402, prepares a loop circuit over which the line relay of the call switch 17 may be controlled in accordance with the operation of the impulse sender 21A provided in the register sender 21. At its contacts 3403, the relay R3400 pre-

pares the operating circuits for the cut-through relay R2620 and the cut-in relay R3320. At its contacts 3404, the relay R3400 prepares a circuit for controlling the supervisory relay R3530 over the E. C. path extending to the call switch 17. At its contacts 3405, the relay R3400 closes a circuit for energizing the start send relay R2650, this circuit extending from ground by way of the contacts 3421 and 3405, C2664, the contacts 2632, and the winding of R2650 to battery. At its contacts 3406, the relay R3400 prepares the operating circuit for the blocked sender relay R2610.

The start sending relay R2650, upon operating, locks to ground over a path which includes the contacts 2654, C2664 and the contacts 3405 and 3421. At its contacts 2651 and 2652, the relay C2650 further prepares the circuit over which impulses may be transmitted to and through the call switch 17 from the impulse sender 21A. At its contacts 2653, the relay R2650 further prepares the E. C. control path over which the supervisory relay R3530 may be controlled from the call switch 17 and any succeeding switch of an established train. At its contacts 2655, the relay R2650 further prepares the operating circuit for the cut-through relay R2620. At its contacts 2656, the relay R2650 further prepares the operating circuit for the blocked sender relay R2610. At its contacts 2657, the relay R2650 completes an obvious path for impressing ground potential upon the test conductor of the trunk extending to the call switch 17.

The sender connect relay R3700, upon operating, closes its contacts 3703 to 3706, inclusive, to connect the four code leads A, B, C and D which extend to the key set 22 through the contacts 3713, 3714, 3715 and 3716 and the contacts 3723, 3724, 3725 and 3726 to the code leads A1, B1, C1 and D1 which extend to the digit registers 21B. At its contacts 3701 and 3702, the relay R3700 connects the pulsing leads C2662 and C2661 through the contacts 3711 and 3712 and the contacts 3721 and 3722 to the pulsing leads E1 and F1 which extend to the impulse sender 21A, thus completing a pulsing circuit between the impulse sender and the call switch 17. When this pulsing circuit is completed and the test conductor of the trunk extending to the call switch 17 is connected to ground, the call switch 17 is automatically conditioned to respond to impulses transmitted thereto from the impulse sender 21A in the manner disclosed in the previously cited patent to Crocker.

At its contacts 3708, the relay R3700, upon operating, prepares a circuit, including the contacts 3717 and 3727 and the E. C. I lead, over which the stop send relay R4310 of the impulse sender 21A is controlled during the extension of a connection from the toll operator switchboard to its destination. At its contacts 3707, the relay R3700 prepares the operating circuit for the sender disconnect relay R3630. At its contacts 3701', the relay R3700 prepares a circuit for energizing the error relay R3410. At its contacts 3709, the relay R3700 completes a circuit for energizing the sender supervisory relay R3640 in series with the lower winding of the sender start relay R4350, this circuit extending from ground by way of the contacts 3709, the winding of R3640, the contacts 3631', 3718 and 3728, the lead T1, the contacts 4382, and the lower winding of R4350 to battery.

The hold relay R3620, in operating, closes its contacts 3622 to prepare a locking circuit for the relay R3630. At its contacts 3621, the relay R3620

further prepares the circuit for energizing the supervisory relay R3530.

When energized in the circuit traced above, the sender supervisory relay R3640 closes its contacts 3641 to complete a circuit for energizing the sender pilot lamp 4125, this circuit extending from ground by way of the contacts 3641, and 3541, C4141, and the filament of the lamp 4125 to battery. When this lamp is energized, the operator attending the No. 1 position of the switchboard 11 is informed that the register sender 21 has been operatively associated with the link 15 occupied with the call and that operation of the key set 22 to register the digits of the directory number designating the desired destination of the call in the digit registers 21B may be started.

The sender start relay R4350 also operates when its lower winding is energized in series with the sender supervisory relay R3640 in the manner explained above. In operating, the relay R4350 closes its contacts 4351 to complete a circuit for energizing the connect relay R4470 of the first digit register 21B, this circuit extending from ground by way of the contacts 4351 and 4347, C4395, the contacts 4425, and the winding of R4470 to battery. In closing its contacts 4351, the relay R4350 also connects the holding lead C4394 to ground and prepares the operating circuit for the transfer relay R4340. At its contacts 4352, the relay R4350 connects the marking lead C4392 to ground and prepares operating and locking circuits for the two relays R4290 and R4300. At its contacts 4353, the relay R4350 prepares the operating circuit for the pulse generating relay R4320. At its contacts 4354, the relay R4350 prepares the operating and locking circuits for the eight relays of the counting relay network shown to the left of Fig. 42. At its contacts 4355, the relay R4350 connects the release lead C4397 to ground.

From the above explanation it will be understood that after the start relay R4350 of the impulse sender 21A is operated, the leads C4397, C4395, C4394 and C4392 are connected to ground in the sender, thereby to prepare the circuits described below over which the keyed digits of the directory number designating the destination of the call are successively registered in the several digit registers 21B. Moreover, the connect relay R4470 of the first digit register is energized over the above-traced circuit in response to the operation of the start relay R4350. In operating, this connect relay closes its contacts 4471, 4472, 4473 and 4474 to prepare the operating circuits for the four code relays A1, B1, C1 and D1. Following the operation of this connect relay, all of the equipment necessary to extend the call has been seized and the register sender required to route the call to its destination is conditioned to respond to operation of the key set 22.

REGISTERING THE DIGITS OF THE CALLED NUMBER

In order to register a digit in one of the digit registers 21B, the operator handling the call at the No. 1 position of the switchboard 11 actuates one of the digit keys of the key set 22. When any one of the ten digit keys is operated in this key set, one or two of the four code leads A, B, C and D will be connected to ground to operate one or two of the code relays in the particular digit register which has been set up to receive the digit. The one or two of the code leads connected to ground in the key set 22 depends upon the numerical value of the digit to be registered. It is noted, moreover, that as the digit keys of

the key set 22 are successively operated, the digits designated thereby are successively registered in different ones of the nine digit registers, a transfer operation being effected at the end of each digit registration in one register to set up the next succeeding register to receive the next digit. Thus, after a first digit has been registered in the digit register comprising the four code relays A1, B1, C1 and D1, the transfer relay R4420 of this register operates to set up the second register comprising the four code relays A2, B2, C2 and D2 to receive the next digit for registration. With the connect relay of any one of the nine registers operated, the code relays of that register which correspond to the numerical value of the digit will be operated when the digit key of the key set 22 is actuated to connect the corresponding code leads to ground. With the code relays of any register operated, the marking lead corresponding to the numerical value of the register digit is connected to ground. For example, if the code relays A1 and D1 of the first register are operated, the third marking lead M3 is connected to ground over a path which includes the outer make contacts of the relay D1, the outer make contacts of the relay A1, the common marking lead C4392, and the contacts 4343, 4303 and 4352. On the other hand, if the code relays B1 and D1 of the first register are operated, the fifth marking lead M5 is connected to the grounded lead C4392 over a path which includes the make contacts of the relay B1, the inner break contacts of the relay C1, and the make contacts of the relay D1. More generally considered, the following table shows the code and marking leads which are connected to ground and the code relays which are operated for each digit.

Digit key operated	Code leads marked	Marking leads grounded	Code relays operated		
			First digit	Second digit	Third digit
45 1.....	A1, B1	M1	A1, B1	A2, B2	A3, B3
2.....	A1, C1	M2	A1, C1	A2, C2	A3, C3
3.....	A1, D1	M3	A1, D1	A2, D2	A3, D3
4.....	B1, C1	M4	B1, C1	B2, C2	B3, C3
5.....	B1, D1	M5	B1, D1	B2, D2	B3, D3
6.....	C1, D1	M6	C1, D1	C2, D2	C3, D3
7.....	A1	M7	A1	A2	A3
50 8.....	B1	M8	B1	B2	B3
9.....	C1	M9	C1	C2	C3
0.....	D1	None	D1	D2	D3

To consider the manner in which the different digit registers are set up to receive the successively keyed digits of the directory number designating the destination of the call, it may be assumed that the digit key 4 is first operated in the key set 22, whereby the code leads B1 and C1 are connected to ground to energize the code relays B1 and C1 through the contacts 4474 and 4473 of the connect relay R4470. In operating, the code relay B1 locks to the grounded lead C4397 over a path which includes its inner preliminary make contacts, the winding of R4420, and the contacts 4413. The code relay C1, in operating, locks to the grounded lead C4397 over a similar path. When these locking circuits are completed the winding of the transfer relay R4420 is short-circuited over a path which includes the grounded code leads B1 and C1, the contacts 4474 and 4473, the locking make contacts of the code relays B1 and C1, the contacts 4413, and the grounded release lead C4397. In operating, the two code relays B1 and C1 also function to connect the grounded common marking lead C4392 to the fourth marking lead M4.

When the digit key 4 of the key set 22 is released by the operator, the two code leads B1 and C1 are disconnected from ground, permitting the transfer relay R4420 to be energized in series with the parallel connected windings of the two code relays B1 and C1. These two code relays remain operated when energized in series with the transfer relay R4420. In operating, the relay R4420 opens its contacts 4425 to deenergize the connect relay R4470 of the first register, and closes its contacts 4426 to complete a circuit including the grounded lead C4395 and the contacts 4534 for energizing the connect relay R4480 of the second register. At its contacts 4422, the relay R4420 completes the prepared operating circuit for the slow-acting hold relay R4380, this circuit extending from the grounded release lead C4397 by way of the contacts 4422, the hold lead C4396, and the winding of R4380 to battery.

The connect relay R4470 of the first register, upon restoring, opens its contacts 4471 to 4478, inclusive, thereby to prevent the code relays A1, B1, C1 and D1 of the first register from responding to further operation of the digit keys in the key set 22. The connect relay R4480 of the second register, upon operating, closes its contacts 4481 to 4484, inclusive, whereby the four code relays A2, B2, C2 and D2 of the second register may be selectively energized over the four code leads A1, B1, C1 and D1.

It will be understood that with the connect relay R4480 of the second register operated, the second digit is registered in this register, and that when the digit key of the key set 22 is released to end the registration the operated code relay or relays of the second register are locked energized in series with the transfer relay R4450. With one or two of the code relays A2, B2, C2 and D2 operated, a marking path is prepared for impressing ground potential upon the one of the marking leads M1 to M9, inclusive, which corresponds to the numerical value of the digit registered. The transfer relay R4450 operates when energized in series with one or two of the four associated code relays. In operating, this relay opens its contacts 4454 to deenergize the connect relay R4480, and closes its contacts 4453 to energize the connect relay R4530 of the third register in a circuit which includes the contacts 4428 and the grounded lead C4395 or the contacts 4414 and the grounded lead C4397. At its contacts 4452, the relay R4450 shunts the corresponding contacts 4422 of the first transfer relay R4420 to provide a multiple circuit for energizing the hold relay R4380.

The connect relay R4480, upon restoring, opens its contacts 4481 to 4484, inclusive, to disconnect the four associated code relays from the four code leads A1, B1, C1 and D1. The connect relay R4530, upon operating, closes its contacts 4531 to 4534, inclusive, to prepare the operating circuits for the four code relays A3, B3, C3 and D3, whereby the third digit may be registered in the third register.

With the connect relay R4530 operated, the third digit of the directory number designating the destination of the call is registered in the third register. In this case one or two of the four code relays A3, B3, C3 and D3 are operated in response to the operation of the third actuated digit key in the key set 22. In operating, the code relay or relays lock to the grounded release lead C4397 through the winding of the transfer relay R4520 and the contacts 4513, and in so doing short-circuit the winding of the indicated trans-

fer relay. Also, when one or two of the code relays in the third register are operated, a marking path is prepared over which one of the marking leads M1 to M9, inclusive, may be connected to the grounded marking lead C4393. When the digit key is released in the key set 22, the path short-circuiting the winding of the transfer relay R4520 is broken, permitting this relay to be energized in series with the associated operated code relay or 10 relays. In operating, the transfer relay R4520 opens its contacts 4525 to deenergize the connect relay R4530, and closes its contacts 4524 to energize the connect relay of the fourth register. At its contacts 4522, the relay R4520 shunts the contacts 4422 and 4452, thereby to provide a multiple circuit for maintaining the hold relay R4380 energized.

The manner in which the fourth, fifth, and succeeding digits as keyed up on the key set 22 are registered in the fourth, fifth, and succeeding registers will be clearly apparent from the preceding explanation. In the illustrated arrangement, nine digit registers are provided so that the registering equipment may hold as many as nine digits at any one time. Provisions are made, however, whereby the tenth and following digits may be registered in the first and following registers in the event the desired destination of the call requires the registration of more than nine digits.

30 In this regard it is pointed out that the impulse sender operates to start transmitting the impulses of the first digit immediately this digit is registered in the first register, and normally the transmission of the first digit by the impulse sender 21A will be completed before the ninth digit is registered in the ninth register. Incident to the transmission of the first digit as registered in the first register, this register is released in the manner pointed out below. Also incident to the transmission of the first digit, the transfer relay R4340 operates to disconnect the lead C4395 from ground and thus prevent the reoperation of the connect relay R4470 when the transfer relay R4420 restores. After the lead C4395 is disconnected from ground, the connect relays of the registers are energized through the contacts 4444, 4514, etc., of the transfer relays over the grounded release lead C4397. In operating, the transfer relay R4340 also disconnects the common marking lead C4392 from ground to prevent any of the nine marking leads from being prematurely connected to ground through the marking contacts of the code relays in the first register in the event a tenth digit is registered therein. Thereafter and when the transfer relay of the ninth register is operated 55 incident to the registration of the ninth digit in this register, a circuit including the contacts 4425 and the conductor C4571 is completed for energizing the connect relay R4470. This circuit is extended from the conductor C4571 to the grounded release conductor C4397 through the lower make contacts of the sequence relay in the register last cleared of a digit registered therein, and the lower make contacts of the transfer relays in the succeeding registers. Thus if the sequence relay R4510 of the third register was last operated at the time the transfer relay of the ninth register operates, the operating circuit for the first connect relay R4470 is extended to the 60 grounded release lead C4397 through the contacts 4514 and the make contacts of the transfer relays in each of the fourth to tenth registers. A circuit including the conductor C4573 is also provided through the make contacts of the sequence relay in the ninth register for connecting one of 70 75

the marking leads M1 to M9, inclusive, to ground through the marking contacts of the code relays A1, B1, C1 and D1 of the first register. An additional circuit including the conductor C4574 is provided for energizing the release relay R4400 under the control of the sequence relay in the ninth register.

With the connect relay R4470 energized, the tenth digit may be registered in the first register in an obvious manner, and after this registration is completed the transfer relay R4420 is operated to extend the grounded conductor C4571 through the contacts 4424 and 4454 to the winding of the connect relay R4480 in the second register, whereby this connect relay is energized to condition the second register to receive the eleventh digit. From the above explanation it will be understood that an indefinite number of digits may be stored in the nine digit registers which are provided. This statement is, of course, based on the assumption that all of the nine registers are not occupied with registered digits at the same time.

OPERATION OF THE IMPULSE SENDER

As indicated above, the hold relay R4380 is energized in response to the operation of the relay R4420 immediately after a digit has been registered in the first register, and remains energized so long as any one of the registers has a digit posted therein. In operating, the relay R4380 closes its contacts 4381 to complete an obvious circuit for energizing the start sending relay R4360. At its contacts 4382, the relay R4380 opens the path normally short-circuiting the upper winding of the start relay R4350, whereby this high resistance winding is included in the series circuit for energizing the two relays R4350 and R3640. When its energization is thus decreased, the relay R3640 restores to deenergize the sender pilot lamp 4125 and thus inform the operator handling the call that the sending operation has started.

The start sending relay R4360, upon operating, closes its contacts 4362 to prepare the operating and locking circuits for the eight relays of the counting relay network. At its contacts 4362, the relay R4360 also completes the operating circuit for the pulse generating relay R4320, this circuit extending from ground by way of the contacts 4354, 4308, 4297, 4362, 4286, 4353 and 4316, and the winding of R4320 to battery. In operating, the relay R4320 locks to ground through the contacts 4316 and 4323, and closes its contacts 4321 to complete an obvious circuit for energizing the pulse generating relay R4330. At its contacts 4322, the relay R4320 prepares a locking circuit for the stop relay R4280. The relay R4330, upon operating, closes its contacts 4331 to complete an obvious circuit for energizing the third pulse generating relay R4315. The relay R4315 now operates and opens its contacts 4316 to deenergize the relay R4320, whereby the three relays R4320, R4330 and R4315 are caused to release in the order named and in an obvious manner. The relay R4315, upon restoring, closes its contacts 4316 to recomplete the operating circuit for the relay R4320. Thus a second cycle of operation of the three pulse generating relays is initiated.

The operating cycles of the three pulse generating relays are counted through operation of the relays in the counting relay network. Thus when the relay R4330 first operates, a circuit is completed for energizing the first counting relay R4210, this circuit extending from ground by way of the contacts 4354, 4308, 4297, 4333, 4311, C4275, the contacts 4256, 4248, 4238, 4226 and 4216, and 70 75

the winding of R4210 to battery. In operating, the relay R4330 also functions to complete a path including the conductor C4274 and the contacts 4334 and 4201 for short-circuiting the lower winding of the transfer relay R4200.

When energized in the above-traced circuit the relay R4210 locks to ground over a path including the contacts 4213 and 4223, the lower winding of R4200, C4274 and the contacts 4291, 4308 10 and 4354. A parallel branch of this locking circuit extends from the winding of the relay R4210 through the contacts 4213, 4223, 4201, 4334, 4297, 4308 and 4354 to ground. At its contacts 4211 and 4212, respectively, the relay R4210 prepares two 15 alternative circuits which respectively include the marking leads M1 and M6, over which the stop relay R4280 may be energized in the manner pointed out below. At its contacts 4214, the relay R4210 prepares the operating circuit for the second counting relay R4220. At its contacts 4215, the relay R4210 completes an alternative locking circuit for itself, this circuit extending from ground by way of the contacts 4354, 4308, 4297, 4333, 4311, C4275, the contacts 4204 and 4215, and the winding of R4210 to battery. At its contacts 4216, the relay R4210 opens a point in its operating circuit as traced above.

As the first cycle of operation of the three pulse generating relays R4315, R4320 and R4330 progresses, the relay R4330 restores and opens its contacts 4333 to interrupt the alternative locking circuit for the relay R4210 as traced above. At its contacts 4334, the relay R4330 also opens the path short-circuiting the lower winding of the transfer relay R4200. In response to the latter operation, the lower winding of the transfer relay R4200 is energized in series with the winding of the first counting relay R4210 over a circuit which extends to ground through the contacts 4354. The current traversing this circuit is sufficient to maintain the relay R4210 in its operated position and to cause the operation of the transfer relay R4200. In operating, the relay R4200 closes its contacts 4202 to prepare an alternative locking circuit for itself. At its contacts 4203, the relay R4200 further prepares the operating circuit for the second counting relay R4220. At its contacts 4204, the relay R4200 opens one of the above-traced but now incomplete locking circuits for the first counting relay R4210.

When the relay R4330 operates during the second cycle of operation of the three pulse generating relays, the operating circuit for the second counting relay R4220 is completed, this circuit extending from ground by way of the contacts 4354, 4308, 4297, 4333, 4311, 4203 and 4214, and the winding of R4220 to battery. In operating the second time, the relay R4330 also completes the prepared locking circuit for the transfer relay R4200, this circuit extending from ground by way of the contacts 4354, 4308, 4297, 4334 and 4202, and the upper winding of R4200 to battery. The relay R4220, upon operating, locks to the grounded lead C4274 over a path including the contacts 4224 and 4333. At its contacts 4225, the relay R4220 prepares the operating circuit for the third counting relay R4230. At its contacts 4226, the relay R4220 opens another point in the above-traced operating circuit for the relay R4210. At its contacts 4223, the relay R4220 opens the established locking circuit for the relay R4210, causing the latter relay to restore. At its contacts 4221 and 4222, the relay R4220 prepares two alternative circuits which respectively include the marking leads M2 and M7 over which the stop

relay R4280 may be energized. The relay R4210, upon restoring, opens its contacts 4213 further to interrupt its own locking circuit and the circuit for energizing the lower winding of the transfer relay R4200. At its contacts 4214, the relay R4210 interrupts the operating circuit for the relay R4220. At its contacts 4216, the relay R4210 reprepares its own operating circuit. At its contacts 4211 and 4212, the relay R4210 opens the prepared circuits including the marking leads M1 and M8 over which the stop relay R4280 may be energized.

When the relay R4330 restores during the second operating cycle of the pulse generating relays, the above-traced locking circuit for the transfer relay R4200 is opened at the contacts 4334. The relay R4200 accordingly restores and closes its contacts 4204 further to prepare the operating circuit for the third counting relay R4230. At its contacts 4203, the relay R4200 opens another point in the operating circuit for the second counting relay R4220. At its contacts 4202, the relay R4200 opens another point in its own locking circuit. At its contacts 4201, the relay R4200 reprepares the path for short-circuiting its lower winding.

When the relay R4330 operates during the third operating cycle of the pulse generating relays, the third counting relay R4230 is energized in its operating circuit which may now be traced as extending from the grounded lead C4275 by way of the contacts 4204 and 4225, and the winding of R4230 to battery. In operating the third time, the relay R4330 also closes its contacts 4334 to short-circuit the lower winding of the transfer relay R4200.

The relay R4230, in operating, locks to the grounded lead C4274 over a path which includes the contacts 4234 and 4243, and the lower winding of the transfer relay R4200. At its contacts 4235, the relay R4230 prepares the operating circuit for the fourth counting relay R4240. At its contacts 4236, the relay R4230 opens another point in the operating circuit for the first counting relay R4210. At its contacts 4231 and 4232, the relay R4230 prepares circuits which respectively include the marking leads M3 and M8 over which the stop relay R4280 may be energized. At its contacts 4233, the relay R4230 interrupts the locking circuit for the relay R4220, causing the latter relay to restore. In releasing, the relay R4220 opens its contacts 4224 further to interrupt its own locking circuit, closes its contacts 4223 to reprepare the locking circuit for the first counting relay R4210, and closes its contacts 4226 to reprepare the operating circuit for the relay R4210. At its contacts 4221 and 4222, the relay R4220 opens the prepared circuits including the marking leads M2 and M7 over which the stop relay R4280 may be energized.

When the relay R4330 restores during the third operating cycle of the pulse generating relays, the two paths short-circuiting the lower winding of the transfer relay R4200 are interrupted at the contacts 4333 and 4334, respectively. Incident to this operation, the lower winding of the relay R4200 is energized in series with the third counting relay R4230. In reoperating, the relay R4200 again closes its contacts 4202 to reprepare its own locking circuit, and closes its contacts 4203 further to prepare the operating circuit for the fourth counting relay R4240.

When the relay R4330 operates during the fourth cycle of the three pulse generating relays, it recloses its contacts 4334 to again complete the

locking circuit for the transfer relay R4200, and closes its contacts 4333 to complete the prepared operating circuit for the fourth counting relay R4240. The latter circuit may now be traced as extending from the grounded lead C4275 by way of the contacts 4203 and 4335, and the winding of R4240 to battery. In operating, the relay R4240 locks to the grounded lead C4274 through the contacts 4244 and 4283, and closes its contacts 4245 to prepare the operating circuit for the fifth counting relay R4250. At its contacts 4246, the relay R4240 opens another point in the incomplete operating circuit for the first counting relay R4210. At its contacts 4241 and 4242, the relay R4240 prepares two alternative circuits which respectively include the marking leads M4 and M9 over which the stop relay R4280 may be energized. At its contacts 4243, the relay R4240 interrupts the circuit over which the stop relay R4280 may be energized. At its contacts 4248, the relay R4240 is energized in series with the lower winding of the relay R4200. When this circuit is broken the relay R4230 restores. In releasing, the relay R4230 opens its contacts 4235 to interrupt the operating circuit for the relay R4240, closes its contacts 4236 further to prepare the operating circuit for the relay R4210, and closes its contacts 4233 to reprepare the locking circuit for the relay R4220. At its contacts 4234, the relay R4230 opens another point in its own locking circuit. At its contacts 4231 and 4232, the relay R4230 opens the prepared circuits which respectively include the marking leads M3 and M8 over which the stop relay R4280 may be energized.

When the relay R4330 restores during the fourth operating cycle of the three pulse generating relays, the locking circuit for the transfer relay R4200 is opened at the contacts 4334. The transfer relay now restores and closes its contacts 4204 further to prepare the operating circuit for the fifth counting relay R4250.

When the relay R4330 operates during the fifth operating cycle of the three pulse generating relays, the contacts 4333 are reclosed to complete the prepared operating circuit for the fifth counting relay R4250, this circuit extending from the grounded lead C4275 by way of the contacts 4204 and 4245, and the winding of R4250 to battery. In operating, the relay R4250 locks to the grounded lead C4275 over a path which includes the contacts 4255 and 4204. At its contacts 4254, the relay R4250 completes an obvious circuit for energizing the reflex relay R4280. At its contacts 4256, the relay R4250 opens another point in the operating circuit for the relay R4210. At its contacts 4251, the relay R4250 prepares a circuit including the marking lead M5 over which the stop relay R4280 may be energized. At its contacts 4252, the relay R4250 prepares an alternative circuit for energizing the stop relay. At its contacts 4253, the relay R4250 interrupts the above-traced locking circuit for the fourth counting relay R4240. The latter relay now restores and opens its contacts 4245 to interrupt the operating circuit for the relay R4250. At its contacts 4244, the relay R4240 opens another point in its own locking circuit. At its contacts 4243, the relay R4240 reprepares the locking circuit for the relay R4230. At its contacts 4248, the relay R4240 reprepares the operating circuit for the relay R4210. At its contacts 4241 and 4242, the relay R4240 opens the two prepared circuits including the marking leads M4 and M9 over which the stop relay R4280 may be energized.

The reflex relay R4280, upon operating, closes its contacts 4261 to complete an obvious path for

short-circuiting the winding of the transfer relay R4270. Shortly following the operation of the relay R4260 and during the continued operation of the three pulse generating relays, the relay R4330 restores and opens its contacts 4333 to interrupt the locking circuit for the fifth counting relay R4250. In releasing, the relay R4250 opens its contacts 4251 and 4252 to interrupt the prepared operating circuits for the stop relay R4280, and closes its contacts 4253 to reprepare the locking circuit for the fourth counting relay R4240. At its contacts 4255, the relay R4250 opens another point in its own locking circuit. At its contacts 4256, the relay R4250 reprepares the operating circuit for the first counting relay R4210. At its contacts 4254, the relay R4250 opens the path short-circuiting the winding of the transfer relay R4270, permitting this winding to be energized in series with the winding of the relay R4260 over a circuit which includes the grounded conductor C4274 and the contacts 4261. The current traversing this circuit is sufficient to maintain the reflex relay R4260 operated and to cause the operation of the transfer relay R4270. In operating, the transfer relay R4270 closes its contacts 4272 to prepare the five circuits which respectively include the sixth to ninth marking leads M6 to M9, inclusive, and the contacts 4252, over which the stop relay R4280 may be energized. At its contacts 4271, the relay R4270 opens a point in the common portion of the five circuits which respectively include the first to fifth marking leads M1 to M5, inclusive, over which the stop relay R4280 may be energized.

Following the operation of the transfer relay R4270 and during the continued operation of the three pulse generating relays, the transfer relay R4200 coacts with the five counting relays to count the sixth to tenth impulses of a ten impulse train. The manner in which these relays respond to the operation of the pulse generating relay R4330 during the sixth to tenth operating cycles of the three pulse generating relays is exactly the same as described above with reference to the counting of the first to fifth impulses.

When the fifth counting relay R4250 operates the second time to count the tenth cycle of operation of the three pulse generating relays, it closes its contacts 4252 to complete a circuit through the contacts 4272 for energizing the stop relay R4280. In operating, the relay R4280 locks to ground over a path including the contacts 4282 and 4322. At its contacts 4281, the relay R4280 completes a path including the additional contacts 4301 and 4341 for impressing ground potential upon the lead C4390, thereby to energize the release relay R4400 of the first digit register. At its contacts 4283, the relay R4280 completes the prepared operating circuit for the digit space relay R4290, this circuit extending from ground by way of the contacts 4352, 4283 and 4305, and the winding of R4290 to battery. At its contacts 4284, the relay R4280 opens a point in an incomplete locking circuit for the two relays R4290 and R4300. At its contacts 4285, the relay R4280 opens a point in the operating circuit for the relay R4300. At its contacts 4286, the relay R4280 interrupts the previously traced operating circuit for the relay R4320.

The relay R4290, upon operating, closes its contacts 4291 to complete an obvious multiple circuit for energizing the start sending relay R4360. At its contacts 4292, the relay R4290 prepares the locking circuit for itself and the relay R4300. At its contacts 4294, the relay R4290 pre-

pares the operating circuit for the stop send relay R4310. At its contacts 4295, the relay R4290 opens a multiple point in the common portion of the previously traced operating circuits for the five counting relays. At its contacts 4293, the relay R4290 prepares the operating circuit for the relay R4300. At its contacts 4297, the relay R4290 disconnects the locking conductor C4274 from ground. At its contacts 4296, the relay R4290 prepares an alternative path for impressing ground potential upon this locking conductor.

When the locking conductor C4274 is disconnected from ground, the operating and locking circuits for the fifth counting relay R4250 are opened, causing this relay and the two relays R4260 and R4270 to restore. Thus the relays of the counting network are all released.

During the final portion of the tenth operating cycle of the three pulse generating relays, the relay R4320 restores and opens its contacts 4322 to interrupt the locking circuit for the stop relay R4280. The relay R4280 now restores and opens its contacts 4281 to disconnect the lead C4390 from ground and thus interrupt the operating circuit for the release relay R4400 of the first digit register. At its contacts 4282, the relay R4280 opens another point in its own locking circuit. At its contacts 4286, the relay R4280 reprepares the operating circuit for the pulse generating relay R4320. At its contacts 4285, the relay R4280 completes the prepared operating circuit for the relay R4300, this circuit extending from ground by way of the contacts 4352, 4285 and 4293, and the lower winding of R4300 to battery. At its contacts 4284, the relay R4280 completes a circuit for energizing the upper winding of the relay R4300 in series with the relay R4290, this circuit extending from ground by way of the contacts 4352 and 4284, the upper winding of R4300, the contacts 4292, and the winding of R4290 to battery. After the last-mentioned circuit is completed the relay R4280 opens its contacts 4283 to interrupt the operating circuit for the relay R4290.

The relay R4300, upon operating, opens its contacts 4305 further to interrupt the operating circuit for the relay R4290, and closes its contacts 4304 to prepare a locking circuit for itself. At its contacts 4301, the relay R4300 opens another point in the above-traced path for impressing ground potential upon the lead C4390. At its contacts 4302, the relay R4300 prepares a circuit including the marking lead M7 for energizing the stop relay R4280 during the operation of the counting relays and the pulse generating relays to measure an inter-digit spacing interval between the first and second digits. At its contacts 4303, the relay R4300 disconnects the common marking lead C4392 from ground. At its contacts 4306, the relay R4300 shunts the pulsing contacts 4332 of the pulse generating relay R4330, thereby to prevent current pulses from being transmitted over the pulsing leads E1 and F1 during the inter-digit spacing interval. At its contacts 4308, the relay R4300 opens another point in the initially traced path for impressing ground potential upon the pulsing and locking leads C4275 and C4274. At its contacts 4307, the relay R4300 connects the lead C4274 to ground over an alternative path which includes the contacts 4296, 4312 and 4354, and prepares an alternative path for connecting the pulsing lead C4275 to ground through the pulsing contacts 4333 of the pulse generating relay R4330.

Following the operation of the relay R4300, the three pulse generating relays, operating in conjunction with the relays of the counting network, function to measure the interdigit spacing interval. In this regard it will be noted that the impulse sender has at this time completed its operation to produce ten impulses which are repeated by the relay R4330 over the pulsing leads E1 and F1 to the line relay of the call switch 17. More specifically, during each cycle of operation of the pulse generating relays, the relay R4330 is operated for an interval and during this interval the path normally bridging the pulsing leads E1 and F1 is opened at the contacts 4332. Accordingly, a train of ten impulses is transmitted to the line relay of the call switch 17 during the operation of the impulse sender 21A to transmit the digit "0" as registered in the first digit register.

As pointed out in the above explanation, the lead C4390 is connected to ground during the interval when the stop relay R4280 is energized, i. e., that interval immediately following the transmission of the ten impulses comprising the first digit. It will also be recalled that when the relay R4300 operates, the marking lead C4392 is disconnected from ground in the impulse sender 21A, thereby to prevent marking ground potential from being impressed upon any one of the nine marking leads M1 to M9, inclusive, over a path including this lead and the marking contacts controlled by the code relays of the first register. When the lead C4390 is connected to ground, the release relay R4400 is energized in an obvious circuit, and closes its contacts 4401 to short-circuit the winding of the sequence relay R4410 over a path which includes the contacts 4442, the lead C4394, and the upper winding of the transfer relay R4340. Thereafter and when the stop relay R4280 releases, the path short-circuiting the sequence relay R4410 is opened at the contacts 4281, permitting this relay and the upper winding of the transfer relay R4340 to be energized in series with the relay R4400 in a circuit which extends from ground by way of the contacts 4351, the upper winding of R4340, C4394, the contacts 4442, the winding of R4410, the contacts 4401, and the winding of R4400 to battery. When energized in this circuit, the relay R4410 closes its contacts 4411' to prepare a path from the marking lead C4393 through the marking contacts of the code relays in the second register for impressing ground potential upon the one of the marking leads M1 to M9, inclusive, which corresponds to the setting of the code relays in this register. At its contacts 4411, the relay R4410 prepares the operating circuit for the release relay R4430. At its contacts 4412, the relay R4410 opens a point in the locking circuit for the sequence and release relays provided in the ninth and last register, causing these relays to restore if operated. At its contacts 4413, the relay R4410 deenergizes the transfer relay R4420 and the operated one or ones of the four code relays A1, B1, C1 and D1 in the first register. At its contacts 4414, the relay R4410 prepares one of the previously mentioned multiple circuits over which the connect relays of the various registers may be energized.

The transfer relay R4420, in releasing, opens its contacts 4422 to interrupt one of the multiple circuits for energizing the hold relay R4380. At its contacts 4424, the relay R4420 opens the initially traced circuit for energizing the connect relays of the second and succeeding registers.

At its contacts 4425, the relay R4420 reprepares the operating circuit for the connect relay R4470. The operated one or ones of the code relays A1, B1, C1 and D1, in restoring, function to open the established marking path through the marking contacts of these four relays and also further to interrupt their respective locking circuits. From the above explanation it will be understood that the release and sequence relays R4400 and R4410 of the first register are operated immediately following the transmission of the first digit by the impulse sender 21A. These relays remain operated until they are released under the control of the sequence relay in the second register or until the hold lead C4394 is disconnected from ground in the impulse sender 21A.

As indicated above, the upper winding of the transfer relay R4340 is energized in series with the two relays R4400 and R4410 incident to the operation of the stop relay R4280 to disconnect the lead C4390 from ground. When thus energized, the relay R4340 closes its preliminary make contacts 4346 to complete a locking circuit for itself which includes its lower winding and the contacts 4351. After this locking circuit is completed, the relay R4340 closes its contacts 4345 to short-circuit its upper winding and thus increase the current flow through the series connected relays R4400 and R4410. At its contacts 4347, the relay R4340 disconnects the lead C4395 from ground, thereby to interrupt the circuit initially provided for energizing the connect relays of the various registers. At its contacts 4348, the relay R4340 opens another point in the path for impressing ground potential upon the lead C4390. At its contacts 4342, the relay R4340 prepares a path for impressing ground potential upon the lead C4391. At its contacts 4343, the relay R4340 opens another point in the previously traced path for impressing ground potential upon the marking lead C4392. At its contacts 4344, the relay R4340 prepares a path for impressing ground potential upon the marking lead C4393. Thus following the operation of the transfer relay R4340, control of the marking paths through the marking contacts of the code relays in the second and succeeding registers is transferred from the marking lead C4392 to the marking lead C4393, and control of the sequence and release relays in the different registers is transferred from the lead C4390 to the lead C4391.

As indicated above, the relay R4300, upon operating, reprepares the operating circuit for the relays of the counting network and recloses the circuit over which the pulse generating relay R4320 may be energized. Accordingly, operation of the three pulse generating relays and the relays of the counting network is again initiated. After seven operating cycles of the three pulse generating relays R4315, R4320 and R4330 are counted through operation of the counting relay network, the two relays R4270 and R4220 are energized in the manner previously explained. The relay R4220, upon operating, completes the prepared circuit for energizing the stop relay R4280, this circuit extending from ground by way of the contacts 4302, the seventh marking lead M7, the contacts 4221 and 4272, and the winding of R4280 to battery. In operating, the relay R4280 locks to ground through the contacts 4282 and 4322, and closes its contacts 4283 to complete an alternative locking circuit for the relay R4300, this circuit extending from ground by way of the contacts 4352, 4283 and 4304, and the lower wind-

ing of R4300 to battery. At its contacts 4281, the relay R4280 further prepares the above-mentioned path for impressing ground potential upon the transfer lead C4391. At its contacts 4284 and 4285, the relay R4280 opens the initially completed operating and locking circuits for the two relays R4290 and R4300. The relay R4280 now restores and opens its contacts 4291 to interrupt the multiple circuit for energizing the start sending relay R4360. At its contacts 4292, the relay R4280 opens another point in the locking circuit for itself and the relay R4300. At its contacts 4293, the relay R4290 opens another point in the operating circuit for the relay R4300. At its contacts 4294, the relay R4290 opens the prepared operating circuit for the stop relay R4310. At its contacts 4295, the relay R4290 reprepares the multiple point in the common portion of the operating circuits for the five counting relays of the counting network. At its contacts 4296, the relay R4290 disconnects the locking conductor C4274 from ground, thereby to deenergize the operated relays R4220, R4260 and R4270 of the counting network. At its contacts 4297, the relay R4290 reprepares the initially completed path for connecting the conductor C4274 to ground. When the three relays R4220, R4260 and R4270 restore, the operating circuit for the stop relay R4280 is opened and the counting network is conditioned to count the impulses of the second digit as registered in the second digit register shown in Fig. 44 of the drawings.

Shortly after the counting relay network is released and when the seventh operating cycle of the three pulse generating relays is completed, the relay R4320 restores to interrupt the locking circuit for the stop relay R4280. In releasing, the relay R4280 opens its contacts 4283 to deenergize the relay R4300. At its contacts 4281, the relay R4280 opens the prepared path for impressing ground potential upon the transfer lead C4391. At its contacts 4284 and 4285, the relay R4280 reprepares the previously traced operating and locking circuits for the relays R4290 and R4300. At its contacts 4286, the relay R4280 reprepares the operating circuit for the pulse generating relay R4320.

The relay R4300, in releasing, closes its contacts 4305 further to prepare the operating circuit for the relay R4290, and opens its contacts 4304 further to interrupt its own locking circuit. At its contacts 4306, the relay R4300 opens the path shunting the pulsing springs 4332 of the pulse generating relay R4330, thereby to condition the impulse sender to transmit the impulse or impulses of the second digit over the pulsing leads E1 and F1 to the call switch 17 or a succeeding selector. At its contacts 4308, the relay R4300 completes the initially traced path for impressing ground potential upon the locking conductor C4274 and reprepares the initially traced operating circuits for the five counting relays of the counting network. At its contacts 4301, the relay R4300 further prepares the path for connecting the transfer lead C4391 to ground in the impulse sender 21A. At its contacts 4302, the relay R4300 disconnects the seventh marking lead M7 from ground. At its contacts 4303, the relay R4300 connects the marking lead C4393 to ground, thereby to complete a path through the contacts 4411' and the marking contacts of the code relays in the second register, for impressing ground potential upon the one of the nine marking leads M1 and M9, inclusive, which corresponds to the setting of the indicated code relays. 75

From the foregoing explanation it will be understood that when the relay R4300 restores at the end of the inter-digit spacing interval, operation of the impulse sender 21A to transmit the impulses of the second digit as registered in the second digit register is immediately started, and that a marking path is completed through the marking contacts of the code relays in this register for stopping the counting network of the impulse sender after the number of impulses corresponding to the setting of the second register have been transmitted by the sender. Further to consider the manner in which the counting relays of the impulse sender are controlled, it may be assumed that the digit "4" is registered in the second digit register, such that the code relays B2 and C2 are operated therein. With these two code relays operated a path is completed for impressing ground potential upon the fourth marking lead M4, which includes the contacts 4352, 4303 and 4344, the common marking lead C4393, the contacts 4411', and the inner marking make contacts of the two relays B2 and C2. With the marking lead M4 connected to ground, the stop relay R4280 of the impulse sender is energized in a circuit which includes this lead and the contacts 4242 and 4271 when the fourth counting relay R4240 operates. The stop relay R4280, upon reoperating, again completes the operating circuit for the digit space relay R4290. In closing its contacts 4281, the relay R4280 also connects the transfer lead C4391 to ground, thereby to complete a circuit through the contacts 4411 for energizing the release relay R4430 of the second register. From this point on the manner in which the relays of the impulse sender 21A operate to measure a spacing interval between the second and third digits is exactly the same as described above. In this regard it will be recalled that the two relays R4280 and R4300 remain operated throughout the spacing interval and restore at the end of this interval. It will also be recalled that the stop relay R4280 is deenergized during the initial portion of the spacing interval and restores to disconnect the transfer lead C4391 from ground. Incident to the operation of the relay R4300, the contacts 4303 are opened to disconnect the marking lead C4393 from ground and thus remove ground potential from the fourth marking lead M4. Thus the established marking path through the marking contacts of the four code relays in the second digit register is broken. 50

When the release relay R4430 is energized, it locks to the grounded lead C4394 through its contacts 4431, the winding of R4440, and the contacts 4512, and in so doing short-circuits the winding of the sequence relay R4440. When shortly thereafter the stop relay R4280 restores to disconnect the transfer lead C4391 from ground, the path short-circuiting the winding of the sequence relay R4440 is opened, permitting this relay to be energized in series with the release relay R4430. When thus energized, the relay R4440 operates to deenergize the transfer relay R4450 and the two code relays C2 and B2 of the second register. At its contacts 4441, the relay R4440 prepares the operating circuit for the release relay R4500 of the third register. At its contacts 4444, the relay R4440 prepares the above-described alternative operating circuits for the connect relays of the third and succeeding registers. At its contacts 4441', the relay R4440 prepares a path from the marking lead C4393

through the marking contacts of the code relays in the third register for impressing ground potential upon the one of the marking leads M₁ to M₉, inclusive, which corresponds to the setting of the third register. At its contacts 4442, the relay R4440 deenergizes the series connected release and sequence relays R4400 and R4410 of the first register.

At the end of the inter-digit spacing interval, the two relays R4290 and R4300 are deenergized and restore in the manner previously explained. Incident to the release of the relay R4300, operation of the three pulse generating relays and of the relays in the counting network is again initiated. Also incident to the release of the relay R4300, the contacts 4303 are closed to reconnect the marking lead C4393 to ground, whereby ground potential may be impressed upon one of the nine marking leads M₁ to M₉, inclusive, through the marking contacts of the code relays in the third register. From this point on the manner in which the remaining digits registered in the digit registers 21B are transmitted by the impulse sender 21A, is exactly the same as described above, it being pointed out in this regard that the release and sequence relays of the digit registers are successively operated at the end of the successive digits for the purpose of rendering the counting network of the impulse sender successively controllable by the code relays of the different registers.

Delay between digits

As the call is extended from the link 15 through the call switch 17 and succeeding switches of a toll or local train a switching stage may be reached at which a delay between digits is required which is greater than the normal inter-digit spacing interval. For example, if the call is to be extended over a toll train through a level hunting selector in a distant toll office, a time interval exceeding the normal spacing period between digits is necessary to permit the level hunting selector to complete its required functions. Again, if the call is routed to a switching stage at which a line finder must operate to seize a trunk circuit occupied with the call, a time interval exceeding the normal inter-digit spacing interval may be required in order to permit the finder to find and seize the trunk circuit. In a case of this character, a signal is transmitted back through the switch train to the sender control circuit 20, which results in the E. C. I lead being connected to ground. This signal will be received and ground potential applied to the E. C. I lead during a spacing interval between digits, i. e., at a time when the digit spacing relays R4290 and R4300 are operated. When ground potential is applied to the E. C. I lead, the stop send relay R4310 is energized in a circuit which includes this lead and the contacts 4294. In operating, the relay R4310 opens its contacts 4311 and 4312 to disconnect the two conductors C4275 and C4274 from ground, and to interrupt the operating circuit for the pulse generating relay R4320. Accordingly, when the ensuing cycle of operation of the three pulse generating relays is completed, these relays remain in their respective restored positions. When ground potential is removed from the two conductors C4275 and C4274, the operated relays of the counting network are released. Thus the impulse sender 21A is locked up to prevent the transmission of additional impulses until such time as the stop send relay R4310 is released.

A predetermined interval after the delay or stop-in-dial signal transmitted to the sender control circuit 20 is terminated, the relays of this circuit function to disconnect the E. C. I lead from ground, thereby to deenergize the stop send relay R4310. This relay, in restoring, recloses its contacts 4311 and 4312, thereby to reinitiate the operation of the three pulse generating relays and the relays of the impulse counting network.

10 In this regard it is noted that the operation of the indicated relays to measure a complete spacing interval is started anew when the stop send relay R4310 restores. In other words, seven cycles of operation of the three pulse generating relays must be completed before the impulse sender is conditioned to transmit the impulses of the next digit over the two pulsing leads E₁ and F₁.

Releasing the sender control circuit, the impulse sender and the digit registers

20 After the operator attending the No. 1 position of the switchboard 11 has manipulated the keys of the key set 22 to set up all digits of the directory number designating the destination of 25 the call, she may actuate the disconnect key of this key set to connect the disconnect lead C3644 to ground and thus complete a circuit through the contacts 3707 for energizing the sender disconnect relay R3630. In operating, this relay 30 locks to ground through its preliminary make contacts 3635 and the contacts 3622. At its contacts 3632 and 3633, the relay R3630 shunts the contacts 3701 and 3702, respectively, of the sender connect relay R3700, thereby to complete multiple points in the impulse transmitting circuit. At its contacts 3634, the relay R3630 opens a point in the operating circuits for the cut-through relay R2620 of the link 15 and the cut-in relay R3320 of the position circuit 18. At its 35 contacts 3631, the relay R3630 re completes the circuit for energizing the sender pilot lamp 4125. At its contacts 3636, the relay R3630 shunts the contacts 3708 to provide a multiple path over which the E. C. I lead may be connected to ground. At its contacts 3638, the relay R3630 completes an obvious multiple circuit for energizing the connect relay R3400. At its contacts 3639 and 3631', the relay R3630 substitutes the low resistance winding of the release relay R3610 for the winding of the sender supervisory relay R3640 in the previously traced circuit for energizing the start relay R4350 of the impulse sender 21A. Due to the relatively high resistance of the upper winding of the start relay R4350, the release relay R3610 does not operate when energized in this circuit. At its contacts 3632', the relay R3630 opens a multiple point in one of the operating circuits for the error relay R3410. At its contacts 3633', the relay R3630 deenergizes the sender start relay R3430. At its contacts 3637, the relay R3630 deenergizes the sender connect relay R3700.

The release of the sender start relay R3430 is without effect. The sender connect relay R3700, upon restoring, opens its contacts 3701 and 3702 to interrupt the initially completed impulse transmitting circuit. At its contacts 3703 to 3706, inclusive, the relay R3700 disconnects the four code leads A, B, C and D from the code leads A₁, B₁, C₁ and D₁ extending to the digit registers 21B. At its contacts 3707, the relay R3700 opens a point in the operating circuit for the relay R3630. At its contacts 3708, the relay R3700 opens the initially completed path over 70 which the E. C. I lead may be connected to

ground in the sender control circuit 20. At its contacts 3709, the relay R3700 opens another point in the circuit for energizing the sender supervisory relay in series with the windings of the sender start relay R4350. At its contacts 3701', the relay R3700 opens one of the circuits over which the error relay R3410 may be energized under the control of the error key in the key set 22.

After all of the digits stored in the digit registers 21B have been transmitted by the impulse sender 21A over the pulsing leads E1 and F1, all of the transfer relays R4420, R4450, R4520, etc., in the respective digit registers are released. The last of these transfer relays, upon restoring, disconnects the hold lead C4396 from the grounded release conductor C4397, thereby to deenergize the hold relay R4380. In releasing, the relay R4380 opens its contacts 4381 to interrupt the operating circuit for the start sending relay R4360, but the latter relay is held energized through the contacts 4291 until such time as the digit space relay R4290 and the relay R4300 are deenergized under the control of the counting network, i. e., at the end of a measured spacing interval. At its contacts 4382, the relay R4380 shunts the high resistance upper winding of the start relay R4350 from the established circuit for energizing this relay in series with the release relay R3610 of the sender control circuit 20.

When the energization of the release relay R3610 is thus increased, this relay closes its contacts 3615 to complete an obvious multiple circuit for energizing the connect relay R3400. At its contacts 3614, the relay R3610 opens the operating circuit for the hold relay R3620. At its contacts 3612, the relay R3610 connects the negative pulsing lead C2661 to ground through the winding of the relay R3600, whereby the latter relay may be energized in series with one winding of the line relay in a succeeding switch, in the manner pointed out below. In the usual case, the relay R3609 is not energized in response to operation of the relay R3610. After closing its contacts 3612, the relay R3610 opens its contacts 3613 to interrupt the impulse transmitting circuit. At its contacts 3611, the relay R3610 prepares the operating circuits for the cut-through relay R2620 in the link 15 and the cut-in relay R3320 in the position circuit 18.

Shortly after the relay R3610 operates, the slow-to-release hold relay R3620 releases and opens its contacts 3622 to deenergize the sender disconnect relay R3630. At its contacts 3621, the relay R3620 opens the prepared circuit for energizing the supervisory relay R3530. The sender disconnect relay R3630, upon restoring, closes its contacts 3634 to complete the prepared operating circuit for the cut-through relay R2620, this circuit extending from ground by way of the contacts 3634, 3611, 3601 and 3403, the cut-in lead C2665, the contacts 2655, and the lower winding of R2620 to battery. At its contacts 3635, the relay R3630 opens another point in its own locking circuit. At its contacts 3632 and 3633, the relay R3630 opens two points in the impulse transmitting circuit. At its contacts 3631, the relay R3630 deenergizes the sender pilot lamp 4125. At its contacts 3636, the relay R3630 opens the path over which the E. C. 1 lead may be connected to ground in the sender control circuit 20. At its contacts 3637, the relay R3630 reprepares the operating circuit for the sender connect relay R3700. At its contacts 3638, the relay R3630 opens one of the multiple circuits for en-

ergizing the connect relay R3400. At its contacts 3639, the relay R3630 deenergizes the series connected relays R3610 and R4350, causing both of these relays to restore. At its contacts 3631', the relay R3630 reprepares the circuit for energizing the sender supervisory relay R3640 in series with the windings of the start relay R4350. At its contacts 3632', the relay R3630 reprepares the operating circuit for the error relay R3410. At its contacts 3633', the relay R3630 reprepares the locking circuit for the sender start relay R3430.

The release relay R3610, upon restoring, opens its contacts 3611 to interrupt the operating circuit for the cut-through relay R2620 of the link 15. At its contacts 3612, the relay R3610 disconnects the winding of the relay R3600 from the negative pulsing lead C2661. At its contacts 3613, the relay R3610 reprepares the previously described impulse transmitting circuit. At its contacts 3614, the relay R3610 recompletes the operating circuit for the hold relay R3620. At its contacts 3615, the relay R3610 deenergizes the connect relay R3400. The relay R3400 now restores and opens its contacts 3405 to deenergize the start send relay R2650 of the link 15, and recloses its contacts 3402' to reprepare the operating circuit for the sender start relay R3430. Following the release of the relay R3400, the sender control circuit 20 is fully restored to normal in readiness for further use. In this regard it is noted that the sender start circuit as traced above is opened at the contacts 3231 of the relay R3230 in the operator position circuit 18 before the connect relay R3400 restores. Accordingly, the sender control circuit 20 is not reseized from the position circuit 18 in response to the release of the connect relay R3400.

As indicated above, the sender start relay R4350 is deenergized and restores in response to the release of the sender disconnect relay R3630. Upon restoring, the relay R4350 opens its contacts 4353 and 4354 to interrupt the operating and locking circuits for the pulse generating relay R4320 and the eight relays of the impulse counting network, causing any operated ones of these relays to restore. At its contacts 4352, the relay R4350 opens a point in the previously traced operating and locking circuits for the relays R4290 and R4300. At its contacts 4351, the relay R4350 deenergizes the transfer relay R4340 and disconnects the lead C4394 from ground. At its contacts 4355, the relay R4350 disconnects the release lead C4397 from ground. Following the release of the transfer relay R4340, the impulse sender 21a is fully restored to normal. When ground potential is removed from the release lead C4397 and the lead C4394, the operated relays in the nine registers are all released in an obvious manner.

COMPLETING THE CONNECTION THROUGH THE LINK 15

As indicated above, the cut-through relay R2620 is energized in a circuit which includes the cut-in lead C2665 when the sender disconnect relay R3630 restores. In operating, this relay locks up in a circuit which includes its upper winding, the contacts 2628 and 2567, C2517, and the upper winding of the relay R3230. At its contacts 2628, the relay R2620 also completes a locking circuit for itself which includes the resistor 2655 and its upper winding. At its contacts 2621 and 2622, the relay R2620 connects the negative and positive talking leads of the trunk extending to the call switch 17 to the front talking leads C2572 and C2574 extending through the

operator position circuit 18 to the hybrid coil 2905, whereby the operator headset is operatively connected to the called end of the connection. At its contacts 2623, the relay R2620 opens another point in the path for bridging the terminating impedance comprising the condenser 2517 and the resistor 2518 across the talking leads of the answer switch 16. At its contacts 2629, the relay R2620 completes an obvious multiple path for impressing ground potential upon the control lead of the trunk extending to the call switch 17. At its contacts 2624, the relay R2620 connects the E. C. lead of the call switch trunk to the winding of the front supervisory relay R2600, thereby to permit this relay to be controlled in accordance with the battery or ground termination of the E. C. control path in the switch seized at the distant end of the switch train. At its contacts 2625, the relay R2620 prepares another circuit for energizing the connect relay R2630. At its contacts 2626, the relay R2620 opens a point in the distributor controlled operating circuit for the connect relay R2630. At its contacts 2627, the relay R2620 opens another point in the path for connecting the all-links-busy lead C3045 to ground in the link 15. At its contacts 2621', the relay R2620 completes a multiple path for impressing ground potential upon the link guard lead C3842.

The start send relay R2650, in releasing, opens its contacts 2651, 2652, 2653, 2655 and 2656 to disconnect the sender control leads C2661, C2662, C2663, C2665 and C2666 from the control equipment of the link 15. At its contacts 2654, the relay R2650 opens another point in its own locking circuit. At its contacts 2657, the relay R2650 opens one of the multiple paths for impressing ground potential upon the control lead of the trunk extending to the call switch 17. As indicated above, the relay R3240 of the operator position circuit 18 is energized and operates in response to operation of the cut-through relay R2620 in the answer switch 16. In operating, the relay R3230 opens its contacts 3231 to open a point in the previously traced operating circuit for the sender start relay R3430, thus preventing the sender control circuit 20 from being reseized when the connect relay R3400 releases.

After the call has been extended through the call switch 17 and one or more succeeding switches to a terminating trunk or line circuit in the central office 10 and through the terminating circuit to its destination, which may be a substation served by the central office or one of the distant offices or an operator position in one of the distant trunk connected offices, the E. C. lead of the trunk incoming to the call switch 17 is connected to ground in the terminating trunk circuit. Accordingly when the cut-through relay R2620 operates in the manner pointed out above, a circuit including this lead, the contacts 2624 and the contacts 2533 is completed for energizing the front supervisory relay R2600. In operating, the relay R2600 closes its contacts 2601 to complete a circuit through the contacts 3532 for energizing the front supervisory lamp 2516. The energization of this lamp serves to inform the operator at the No. 1 position of the switchboard that the call has been extended to its destination through the front end of the link 15.

When the call is answered at the called point, certain of the relays of the terminating circuit in the central office operate in the manner explained below to disconnect the E. C. conductor of the trunk incoming to the call switch 17 from ground,

thereby to deenergize the front supervisory relay R2600. This relay, in releasing, opens its contacts 2601 to deenergize the front supervisory lamp 2516. When this lamp is darkened the operator attending the No. 1 position at the switchboard is advised that the call has been answered.

If the routing of the call to the called substation requires the assistance of an inward operator in one of the distant offices, the operator attending the No. 1 position of the switchboard 11, upon observing that the front supervisory lamp 2516 is deenergized, may converse with the answering operator in the called office and repeat the necessary information to the answering operator to enable the call to be extended to the desired substation. In this regard it will be noted that following the operation of the cut-through relay R2620, the line terminals of the hybrid coil 2905 are bridged across the talking conductors of the trunk incoming to the call switch 17 over a channel which includes the contacts 3012 and 3014, the contacts 3101 and 3103, the contacts 3111, the contacts 3151 and 3154, the front talking leads C2574 and C2572, the contacts 2561 and 2564 and the contacts 2621 and 2622. Thus a talking circuit is established between the No. 1 position of the switchboard 11 and the switchboard or substation at which the call is answered. This talking circuit is also extended to include the calling end of the connection over a channel which includes the contacts 3201 and 3204, the rear talking leads C2575 and C2573 and the contacts 2565 and 2562.

After the connection between the calling and called substations has been satisfactorily completed, the operator attending the No. 1 position of the switchboard 11 may disconnect the position circuit 18 from the link 15 by actuating the operator disconnect key 4005. When this key is moved off-normal, the disconnect relay R3030 is energized over a circuit which includes the conductor C4086. In operating, the slow-acting relay R3030 opens its contacts 3031 to deenergize the relay R3040. At its contacts 3032, the relay R3030 opens a point in the operating circuit for the position start relay R3210. At its contacts 3033, the relay R3030 opens a point in the common portion of the operating circuits for the start relays R3310 and R3430.

The relay R3040, upon restoring, opens its contacts 3042 to deenergize the series connected relays R3010 and R2630. At its contacts 3043, the relay R3040 opens another point in its own locking circuit. At its contacts 3044, the relay R3040 opens the shunt across the contacts 3021, thereby to open a point in the common portion of the available operating circuits for the start relays R3310 and R3430.

The relay R3010, in releasing, opens its contacts 3012 and 3014 to disconnect the hybrid coil 2905 from the connection established between the calling and called substations through the link 15. At its contacts 3011 and 3013, the relay R3010 connects one winding of the monitor repeating coil 2906 across the talking circuit as established through the link 15. At its contacts 3015, the relay R3010 prepares one of the operating circuits for the connect relay R2630. At its contacts 3016, the relay R3010 deenergizes the relay R3050. At its contacts 3017, the relay R3010 prepares the operating circuit for the monitor relay R3000. The relay R3050, upon restoring, recloses its contacts 3051 further to prepare one of the operating circuits for the connect relay R2630.

When the operator disconnect key 4005 is re-

leased under the control of the operator attending the No. 1 position of the switchboard, the disconnect relay R3030 is deenergized and restores. In releasing, this relay closes its contacts 3031 to reprepare the operating circuit for the relay R3040, and closes its contacts 3033 to reprepare the operating circuit for the start relay R3310. At its contacts 3032, the relay R3030 reprepares the operating circuit for the start relays R3210 and R3430.

When the previously traced circuit for energizing the relay R3010 in series with the lower winding of the connect relay R2630 is broken at the contacts 3042 of the relay R3040, the connect relay R2630 restores. In releasing, this relay opens its contacts 2631 further to interrupt its own locking circuit and, at its contacts 2632, opens a point in the operating circuit for the start send relay R2650. At its contacts 2633, the relay R2630 deenergizes the connect relay R2560. At its contacts 2636, the relay R2630 opens a point in one of the operating circuits for the call lock relay R3040. At its contacts 2634, the relay R2630 opens the circuit for energizing the link busy lamp 2604 in accordance with the ground pulses being transmitted over the 60 I. P. M. lead C2638. At its contacts 2635, the relay R2630 completes a circuit including the contacts 2612 and 2621' for directly energizing the busy lamp 2604. Thus, following the release of the connect relay R2630, the busy lamp 2604 is continuously energized to indicate that the link 15 is occupied with a call.

The connect relay R2560, upon restoring, opens its contacts 2561, 2562, 2564 and 2565 to disconnect the front and rear talking leads C2572, C2574 and C2573, C2575, respectively, from the line terminals of the repeating coil 2906 in the operator position circuit 18. At its contacts 2563 and 2566, the relay R2560 connects the talking wipers 2401 and 2402 of the answer switch 16 to the talking wipers of the call switch 17, thereby to establish a direct talking circuit between the calling substation and the called substation or operator position. At its contacts 2567, the relay R2560 opens the previously traced circuit for energizing the relay R3230 in series with the upper winding of the cut-through relay R2620. It will be noted that after this circuit is opened the upper winding of the cut-thrown relay is held energized in a circuit which includes the resistor 2555. At its contacts 2568, the relay R2560 opens a point in one of the operating circuits for the relay R2610. At its contacts 2569, the relay R2560 deenergizes the sender seize relay R3250. At its contacts 2561', the relay R2560 deenergizes the start relay R2530.

The relay R2530, upon restoring, closes its contacts 2534 to prepare a circuit including the E. C. conductor of the trunk extending to the call switch 17, over which the front supervisory lamp 2516 may be controlled in response to different supervisory operations performed at the called end of the connection. At its contacts 2533, the relay R2530 opens a point in the operating circuit for the front supervisory relay R2600. At its contacts 2532, the relay R2530 opens the circuit over which the lamp 2516 is controlled by the front supervisory relay R2600. At its contacts 2531, the relay R2530 reprepares the path for bridging the terminating impedance comprising the condenser 2517 and the resistor 2518 across the talking conductors of the answer switch 16. At its contacts 2535, the relay R2530 reprepares the operating circuit for the release rear relay R2510. At its contacts 2538, the relay R2530 deenergizes the

upper winding of the relay R2520. The relay R2520 is, however, held operated due to the continued energization of its lower winding in series with the winding of the cut-off relay in the trunk circuit occupied with the call. At its contacts 2531, the relay R2530 opens a point in the path over which the test wiper 2405 may be connected to ground in the operator position circuit 18. At its contacts 2538, the relay R2530 opens the paths over which ground potential may be impressed upon the E. C. wipers 2407 and 2408 of the answer switch 16. At its contacts 2539, the relay R2530 opens a point in one of the circuits for energizing the rear supervisory relay R2640 and the rear supervisory lamp 2603. At its contacts 2532', the relay R2530 prepares circuits over which the rear supervisory lamp 2603 may be controlled in the manner explained below. At its contacts 2531', the relay R2530 opens a point in the circuit for controlling the rear supervisory relay R3260 of the position circuit 18 through the rear end of the link 15. It will be noted that, following the release of the start relay R2530, the control equipment of the link 15 is wholly disconnected from the operator position circuit 18. Moreover, so long as this link is occupied with the call under consideration, the link guard lead C3842 is connected to ground in the link to prevent the link from being allotted for use by the link distributor 19.

As indicated above, the relay R2560 of the link 15, upon restoring, deenergizes the two relays R3230 and R3250 in the operator position circuit 18. The relay R3230, upon restoring, closes its contacts 3231 further to prepare the operating circuits for the start relays R3310 and R3430. The relay R3250, upon restoring, opens its contacts 3252 to disconnect the link start lead C2580 from ground. At its contacts 3251, the relay R3250 opens a point in the locking circuit for the relay R3340. At its contacts 3253, the relay R3250 further prepares the operating circuit for the position start relay R3210. At its contacts 3254, the relay R3250 reprepares the initially traced path for impressing ground potential upon the link start lead C2580. At its contacts 3255, the relay R3250 opens a point in the previously traced operating circuit for the sender start relay R3430. At its contacts 3257, the relay R3250 reprepares the locking circuit for the accept call relay R2920. At its contacts 3256, the relay R3250 completes the prepared operating circuit for the start relay R3310. Following the operation of the last-mentioned relay, the operator position circuit 18 is marked as idle in the position distributor 13 and the operating circuit for the position start relay R3210 is prepared, so that when the position distributor 13 again operates to select the No. 1 position of the switchboard 11 to receive a call, the position circuit is fully conditioned to accept the call.

SUPERVISION AND KEY CONTROL

After a connection has been established through the link 15 in the manner explained above, the operator attending the No. 1 position of the switchboard may monitor the connection, re-enter the connection for the purpose of conversing with either the calling or called party, split the connection for the purpose of conversing with either the calling or the called party to the exclusion of the other party, or she may split the connection and release either the calling or the called end thereof. Various other supervisory operations may be performed by this operator in the manner pointed out below.

Monitoring the connection

In order to monitor the connection as established through the link 15, the operator attending the No. 1 position of the switchboard may actuate the link monitor key 2540 to its off-normal position wherein the contacts 2541, 2542 and 2543 are respectively engaged. Incident to this operation, the upper winding of the repeating coil 2906 is bridged across the talking circuit established through the link 15 over a path which includes the contacts 3011 and 3013, the contacts 3101 and 3103, the talk monitor leads C2562 and C2561 and the key contacts 2542 and 2541. At the contacts 2543 of the key 2540, a circuit including the lead C2563 and the contacts 3109 and 3017 is completed for energizing the monitor relay R3000. From a consideration of this circuit, it will be understood that the monitor relay R3000 can only be energized through the contacts of the monitor key 2540 during a period when the position circuit 18 is not occupied with a call. Thus so long as this circuit is busy, the switching relay R3010 is operated to hold the operating circuit for the monitor relay R3000 open at the contacts 3017. The relay R3000, upon operating, bridges the receiver 2901 of the operator headset across the lower winding of the repeating coil 2906 over a path which includes the tip contacts of the plug 2903 and the jack 2904, and the contacts 3004 and 3002. At its contacts 3001 and 3003, the relay R3000 opens the path over which the receiver 2901 is normally connected to the hybrid coil 2905. Thus following the operation of the monitor relay R3000, the receiver 2901 is coupled to the talking circuit through the link 15 over a channel which includes the repeating coil 2906. The transmitter 2903 of the operator headset is, however, not operatively associated with the talking circuit extending through the link. Accordingly, the operator attending the No. 1 position of the switchboard can only listen in on the conversation being held over the connection and is prevented from talking over the connection.

When the monitor key 2540 is restored to normal the contacts 2543 thereof are opened to de-energize the monitor relay R3000, and the contacts 2541 and 2542 are opened to interrupt the path over which the upper winding of the repeating coil 2906 is bridged across the talking circuit established through the link 15. The relay R3000, upon restoring, opens its contacts 3002 and 3004 to disconnect the receiver 2901 from the lower winding of the repeating coil 2906, and recloses its contacts 3001 and 3003 to reconnect this receiver to the hybrid coil 2905.

Re-entering the connection

If for any reason the operator handling the call at the No. 1 position of the switchboard desires to re-enter the connection established through the link 15, she may momentarily operate the self-restoring talk key 2550 to its off-normal position wherein the contacts 2551 and 2552 are closed. In this regard it will be understood that if the operator at this position of the switchboard is handling a C. L. R. call she will, as a matter of routine, re-enter the connection for challenging purposes before releasing the switch train through which the connection extends. When the contacts 2551 of the talk key 2550 are engaged, the previously mentioned alternative operating circuit for the connect relay R2630 is completed, this circuit extending from ground by way of the contacts 2911, 3015 and 3107, C2566, 75

the contacts 2551, one of the two sets of contacts 2443 and 2463 and the contacts 2625 in parallel, and the upper winding of R2630 to battery. At the talk key contacts 2552, a circuit is prepared for energizing the call lock relay R3040.

5 The connect relay R2630, in operating, closes its contacts 2631 to reprepare the circuit for energizing its lower winding in series with the switching relay R3010. At its contacts 2635, the relay R2630 opens the circuit for continuously energizing the link busy lamp 2604. At its contacts 2634, the relay R2630 connects the busy lamp to be intermittently energized by the ground pulses transmitted over the 60 I. P. M. lead C2638. At 10 its contacts 2636, the relay R2630 completes the prepared alternative operating circuit for the relay R3040, this circuit extending from ground by way of the contacts 2621' and 2443' in parallel, the contacts 2636, the key contacts 2552, C2571, the contacts 3031, and the winding of R3040 to battery. At its contacts 2633, the relay R2630 completes the operating circuit for the connect relay R2560.

15 The connect relay R2560, in operating, closes its contacts 2567 and 2569 to complete the previously traced operating circuits for the relays R3230 and R3250 of the position circuit 18. At its contacts 2561 to 2565, inclusive, the relay R2560 connects the calling and called ends of the connection together over the front and rear talking leads C2572, C2574 and C2573, C2575 which extend to the operator position circuit 18, and then opens the direct connection between the two ends of the connection.

20 35 The relay R3250, upon operating, opens its contacts 3256 to deenergize the start relay R3310 and, at its contacts 3253, opens a point in the operating circuit for the position start relay R3210. At its contacts 3252, the relay R3250

40 recloses the operating circuit for the start relay R2530. The latter relay, in operating, performs the functions described above. The start relay R3310, in restoring, reconnects the guard lead C3962 to ground, thereby to mark the No. 1 position of the switchboard as busy in the position distributor 13, and opens its contacts 3314 to disconnect the start lead C3963 from ground in the position circuit 18. Thus it will be noted that with the two relays R3230 and R3250 operated

45 50 and the start relay R3310 released in the operator position circuit 18, the No. 1 position of the switchboard can not be assigned by the position distributor 13 to receive another call.

The relay R3040, upon operating, locks to ground through its contacts 3043, and closes its contacts 3042 to complete the previously traced circuit for energizing the switching relay R3010 in series with the lower winding of the connect relay R2630. Following the operation of the

60 65 switching relay R3010, the control equipment of the link 15 and the operator position circuit 18 occupy the settings which prevail prior to the operation of the operator disconnect key 4005. In this regard it will be noted that with the call lock relay R3040 operated, the connect relay R2630 is locked up in series with the relay R3010. Accordingly, the talk key 2550 may be released without disconnecting the position circuit 18 from the link 15. It will also be noted that with the

70 75 switching relay R3010 operated, the front and rear talking leads of the operator position circuit are connected to the line terminals of the hybrid coil 2905. Accordingly, the operator handling the call may converse with either the calling or the called party over the established connection

or may challenge the connection to determine whether or not it is still in use.

In order to disconnect the operator position circuit 18 from the link 15 after the talk key 2550 has been momentarily actuated in the manner explained above, the operator attending the No. 1 position of the switchboard must actuate the operator disconnect key 4005. When this key is momentarily operated, the position circuit 18 is disconnected from the link 15 and is marked as idle in the position distributor 13, in the exact manner explained above.

Switchhook and disconnect supervision

As indicated above, when the connection has been extended through the call switch 17 to the desired operator switchboard or substation, ground potential is returned over the E. C. conductor of the trunk extending to the call switch 17 for the purpose of energizing the front supervisory lamp 2516. Thereafter and when the call is answered at the called substation or operator switchboard, this lead is disconnected from ground in the last switch of the train to cause the deenergization and darkening of the lamp 2516. It is noted that if the call is extended to a substation the answering party is provided with switchhook supervision and may signal the operator attending the No. 1 position of the switchboard 11 by repeatedly operating the switchhook at the called station. Each time the switchhook is operated the E. C. conductor of the trunk extending to the call switch 17 is connected to ground in the last switch of the train, thereby to energize the front signal lamp 2516 in a circuit which includes this lead and the contacts 2624 and 2534. Conversely, each time the switchhook at the answering station is released, the E. C. lead of the trunk extending to the call switch 17 is disconnected from ground to deenergize the lamp 2516. Accordingly, the intermittent operation of the switchhook at the answering station causes the supervisory lamp 2516 to flash, thereby to indicate to the operator handling the call that the party at the called substation desires additional service. If the switchhook supervision is received in the link 15 at a time when this link is connected to the position circuit 18, the front supervisory relay R2600 functions to repeat the ground pulses to the lamp 2516 in a manner which will be clearly apparent from the preceding description. From the above explanation it will also be understood that when the call is released at the called substation or operator position, the E. C. lead of the trunk extending to the call switch 17 is connected to ground in the last switch of the established switch train, whereby the front supervisory lamp 2516 is continuously energized. With this lamp steadily illuminated, the operator handling the call is informed that the called end of the connection as extended from the switchboard 11 is ready to be released.

It will also be recalled from the preceding explanation that the rear supervisory lamp 2603 is not energized in response to the seizure of the link 15 from the common start circuit 12 and normally will remain deenergized until the link is disconnected from the operator position circuit 18 under the control of the start relay R2530. Following the release of the relay R2530, the rear supervisory lamp is connected to be controlled by the link supervisory relay R2520. In this regard it is pointed out above that, following the

release of the start relay R2530, the lower winding of the supervisory relay R2520 is held energized over a circuit which extends by way of one of the test wipers 2405 and 2406 to the particular 5 trunk circuit preceding the answer switch 16 occupied with the call. So long as the call is not released at the calling end thereof, the resistance of this circuit as controlled in the trunk circuit occupied with the call, is maintained at a value 10 sufficiently low to prevent the supervisory relay R2520 from releasing. When, however, the call is released at the calling end thereof, the supervisory relays of the trunk circuit occupied with the call operate to increase the resistance of this 15 circuit by an amount sufficient to cause the release of the supervisory relay R2520. If the connection is immediately re-established at the calling end thereof, the supervisory relays of the trunk circuit function to remove a resistor from the circuit for energizing the lower winding of the supervisory relay R2520, whereby this relay is reoperated. It will be understood, therefore, that if the switchhook is flashed at a calling substation located in the area served by the central office 10, for example, the supervisory relay R2520 20 will alternately restore and reoperate, and that when the call is finally released at the calling substation this relay will remain in its restored position. Each time the supervisory relay R2520 restores it closes its contacts 2521 to complete a circuit for energizing the rear supervisory lamp 2603, this circuit extending from ground by way of the contacts 2484, 2521, 2532', the cam springs 2658, the contacts 2644 and the filament of the lamp 2603 to battery. Each time the relay R2520 25 restores, it also closes its contacts 2522 to prepare a path for short-circuiting its lower winding. This path and the circuit for energizing the rear supervisory lamp 2603 are opened each 30 time the relay R2520 reoperates.

From the above explanation it will be understood that the front and rear supervisory lamps of the link 15 may be controlled through the call switch 17 and the answer switch 16, respectively, 45 to provide both flashing recall signals and steady disconnect signals.

Further to consider the manner in which supervisory signaling over the rear end of the link 15 is handled, it is noted that if the answer switch 16 is operated to seize a ring-down trunk circuit, such, for example, as the trunk circuit 28, to which it has access, the normal post springs 2605 are operated into engagement during the vertical movement of the wipers 2401 to 2409, 50 inclusive. It will be understood in this regard that the normal post springs 2605 are operated when the answer switch wipers are elevated to a position opposite a level of bank contacts in which a group of ring-down trunk circuits is 55 terminated. After the call is completed and when the operator in the distant office transmits a ring-off signal over the trunk 7 to the trunk circuit 28, the ringing relays of this trunk circuit operate to insert a resistor in the circuit 60 over which the lower winding of the relay R2520 is energized. When its energization is thus decreased, the relay R2520 releases to complete the above-traced circuit for energizing the rear supervisory lamp 2603. In closing its contacts 65 2522, the relay R2520 also short-circuits its lower winding through the contacts 2642 and the normal post springs 2605. With this winding short-circuited, the relay R2520 is rendered non-responsive to further operation of the supervisory 70 relays in the trunk circuit 28. Thus, the signal

produced by energization of the lamp 2603 is effectively locked in.

RELEASING THE LINK

When the connection established through the link 15 is released at both the calling and called ends thereof, so that steady disconnect signals are produced by both the rear and front supervisory lamps 2603 and 2516, respectively, the operator may release the link 15 by momentarily operating the link release key 2556. When this key is moved off normal, the contacts 2553 are closed to short-circuit the upper winding of the cut-through relay R2620 over an obvious path and the contacts 2554 are closed to short-circuit the lower winding of the change-over relay R2480 over a path which includes the vertical off-normal springs 2414. Thus the two relays R2480 and R2620 are deenergized and restore.

In releasing, the relay R2480 closes its contacts 2481 to reprepare the path for connecting the all-links-busy lead C3045 to ground in the link 15. At its contacts 2482, the relay R2480 opens a point in the previously traced operating circuit for the tone relay R3110. At its contacts 2483, the relay R2480 completes a circuit through the off-normal springs 2503 and the contacts 2535 for energizing the release rear relay R2510. At its contacts 2484, the relay R2480 opens a point in the previously traced operating circuits for the two test relays R2430 and R2450, and further interrupts the circuit over which the supervisory relay R2520 is controlled after a connection is established through the link. At its contacts 2484, the relay R2480 also deenergizes the rear supervisory lamp 2603 and disconnects from ground the one of the two test wipers 2405 and 2406 which was utilized in the operation of the answer switch to find the calling trunk circuit. When this test wiper is disconnected from ground the trunk circuit occupied with the call is released in the usual manner. At its contacts 2486, the relay R2480 opens a point in the incomplete operating circuit for the rotary magnet 2412. At its contacts 2485, the relay R2480 reprepares the operating circuit for the vertical magnet 2411. At its contacts 2487, the relay R2480 opens a point in its own locking circuit. At its contacts 2488, the relay R2480 reprepares the previously traced circuit for energizing its own upper winding in series with the winding of the step relay R2470.

The release rear relay R2510, upon operating, opens its contacts 2512 to deenergize the operated one of the two switching relays R2440 and R2460. At its contacts 2511, the relay R2510 opens a point in the distributor controlled operating circuit for the connect relay R2630. At its contacts 2514, the relay R2510 completes an obvious alternative path for short-circuiting the lower winding of the change-over relay R2480. At its contacts 2515, the relay R2510 opens a point in the circuit for energizing the upper winding of the change-over relay R2480 in series with the step relay R2470. At its contacts 2513, the relay R2510 completes an obvious circuit for energizing the release magnet 2501. The release of the operated switching relay R2440 or R2460 is without effect.

When the release magnet 2501 is energized, the wipers 2401 to 2409, inclusive, are returned to rotary and vertical normal in the usual manner. Incident to the return movement of these wipers, the off-normal springs 2502 are disengaged to deenergize the release magnet 2501; the off-nor-

mal springs 2504 are moved into engagement to reprepare the distributor controlled operating circuit for the connect relay R2630; the off-normal springs 2503 are disengaged to deenergize the release rear relay R2510; the off-normal springs 2414 are disengaged to open a point in the previously traced holding circuit for the change-over relay R2480; and, if operated, the normal post springs 2605 are opened to interrupt the path short-circuiting the lower winding of the supervisory relay R2520.

The release rear relay R2510, upon restoring, recloses its contacts 2511 further to prepare the distributor controlled operating circuit for the connect relay R2630 and, at its contacts 2512, reprepares the locking circuits for the two switching relays R2440 and R2460. At its contacts 2513, the relay R2510 opens another point in the operating circuit for the release magnet 2501. At its contacts 2514, the relay R2510 opens a point in one of the paths for short-circuiting the lower winding of the change-over relay R2480. At its contacts 2515, the relay R2510 reprepares the circuit for energizing the upper winding of the change-over relay R2480 in series with the step relay R2470.

The cut-through relay R2620, upon restoring, opens its contacts 2621 and 2622 to disconnect the talking conductors of the call switch 17 from the talking conductors of the answer switch 16. At its contacts 2623, this relay closes the path over which the terminating impedance, comprising the condenser 2517 and the resistor 2518, is normally bridged across the talking conductors of the answer switch 16. At its contacts 2624, the relay R2620 deenergizes the front supervisory lamp 2516 and opens a point in the operating circuit for the front supervisory relay R2600. At its contacts 2625, the relay R2620 opens a point in the circuit controlled by the talk key 2560 over which the connect relay R2630 may be energized. At its contacts 2626, the relay R2620 reprepares the distributor controlled circuit for energizing the connect relay R2630. At its contacts 2627, the relay R2620 reconnects the all-links-busy lead C3045 to ground in the link 15. At its contacts 2628, the relay R2620 opens its own locking circuit. At its contacts 2629, the relay R2620 disconnects the test conductor of the trunk extending to the call switch 17 from ground, whereby this switch and the succeeding switches of the train are released in the usual manner. At its contacts 2621', the relay R2620 opens one of the paths for impressing ground potential upon the link guard lead C3842. In this regard it will be noted that after the operated one of the two switching relays R2440 and R2460 and the cut-through relay R2620 are released, the indicated guard lead is disconnected from ground in the link 15, thereby to mark this lead as idle in the link distributor 19. At its contacts 2621', the relay R2620 also deenergizes the busy lamp 2604. Following the release operations just described the link 15 is fully restored to normal.

OPERATOR POSITION KEY CONTROL

In handling calls of different types originating at different points and requiring special service, it is necessary to use all of the key control facilities of the operator position circuit. For example, the operator attending the No. 1 position of the switchboard in handling a C. L. R. call originating in the area served by the central

office 10, may find it necessary to rering the calling subscriber after this subscriber has disconnected. Ringing over the rear end of the link, i. e., through the answer switch 16, may also be necessary in the transmission of supervisory signals to the switchboards of distant manual offices which are connected with the central office 10 over ring-down trunks. For example, in handling a call originating in the manual office No. 1, and routed through the ring-down trunk circuit 28 to the first operator position of the switchboard 11, the operator attending this position may find it necessary to transmit ringing current to this trunk circuit from the operator position circuit 18 for the purpose of signaling the operator handling the call at the switchboard 41 in the distant manual office. Alternatively, the operator attending the No. 1 position of the switchboard 11 may find it necessary to transmit ringing current over the front end of the link, i. e., through the call switch 17, for the purpose of resignaling a called subscriber or for the purpose of transmitting a supervisory signal over a ring-down trunk to a distant manual office.

Ringing—front and rear

In order to transmit ringing current over the talking leads of the call switch 17, i. e., over the front end of the link 15, the operator attending the No. 1 position of the switchboard may actuate the ring front key 4050 to its off-normal position. When this key is moved off normal, a circuit including the contacts 4051 and the lead C4082 is completed for energizing the split call relay R3150, and a circuit is prepared at the contacts 4052 and 4054 for transmitting ringing current over the called end of the connection. At the contacts 4053, a circuit including the lead C4083 is completed for energizing the impedance cut-off relay R3140. In operating, the relay R3140 opens its contacts 3141 to interrupt the path over which the terminating impedance comprising the condenser 3142 and the resistor 3143 may be connected across the front and rear talking leads.

The split call relay R3150, upon operating, opens its contacts 3151 and 3154 to disconnect the front talking leads C2574 and C2572 from the line terminals of the hybrid coil 2905 and from the rear talking leads C2573 and C2575. At its contacts 3152, 3153, 3155 and 3156, the relay R3150 prepares a path for bridging the terminating impedance comprising the resistor 3143 and the condenser 3142 across the front leads C2574 and C2572. At its contacts 3152 and 3155, the relay R3150 completes the circuit for transmitting ringing current over the called end of the connection. This circuit may partially be traced as extending from the ungrounded terminal of the ringing current generator, not shown, by way of the ringing current conductor C4055, the contacts 4054, C4081, the contacts 3155, C2572, the contacts 2561 and 2621, the negative side of the connection extending to the terminating trunk circuit or substation, the supervisory relay or ringer provided in the terminating trunk circuit or substation circuit, the other side of the connection extending to the terminating trunk circuit or substation, the contacts 2622 and 2564, C2574, the contacts 3152, C4080, and the contacts 4052 to the grounded terminal of the ringing current generator.

When the ring front key 4050 is released, the above-traced circuit traversed by the ringing current is first opened at the contacts 4054 and 4052.

At the contacts 4053, the operating circuit for the impedance cut-off relay R3140 is opened. At the contacts 4051, the split call relay R3150 is deenergized. Following the release of the two relays R3140 and R3150 the ringing operation is completed. Since these two relays are directly controlled by the ring front key 4050, it will be understood that the operation of ringing over the front end of the link 15 may be repeated at will and that, if desired, coded ringing current may be transmitted over this end of the link for any required purpose.

In order to transmit ringing current over the rear end of the link 15, the operator at the No. 1 position of the switchboard 11 may actuate the ring rear key 4040. When this key is moved to its off-normal position, a circuit including the contacts 4044 and the lead C4083 is completed for energizing the impedance cut-off relay R3140. At the contacts 4043 and 4042, a circuit is prepared for transmitting ringing current through the answer switch 16. At the contacts 4041, a circuit including the lead C4085 is completed for energizing the split answer relay R3200.

The impedance cut-off relay R3140, in operating, performs the function described above. The split answer relay R3200, upon operating, closes its contacts 3203 and 3206 to prepare a path for bridging the terminating impedance comprising the resistor 3143 and the condenser 3142 across the rear talking leads C2575 and C2573. At its contacts 3201 and 3204, the relay R3200 disconnects the rear talking leads from the front talking leads C2574 and C2572, and also from the line terminals of the hybrid coil 2905. At its contacts 3203 and 3205, the relay R3200 completes the circuit for transmitting ringing current over the rear end of the link 15. One side of this circuit extends from the ungrounded terminal of the ringing current generator by way of the ringing current conductor C4055, the contacts 4043, C4080, the contacts 3205, C2573, the contacts 2562, and the contacts 2441 to the upper talking wiper 2401 of the answer switch. The return side of the established ringing current circuit extends from the grounded terminal of the ringing current generator by way of the contacts 4042, C4089, the contacts 3202, C2575, the contacts 2565, and the contacts 2442 to the lower talking wiper 2402 of the answer switch. From the two talking wipers of the answer switch, the ringing current may be transmitted through the ringer provided at a calling substation or through the supervisory relay of a terminating trunk circuit, depending upon the character of the call in progress.

When the ring front key 4040 is released, the circuit traversed by the ringing current is first broken at the contacts 4042 and 4043. At the contacts 4041 and 4044 the two relays R3200 and R3140 are respectively deenergized. The split answer relay R3200, in releasing, opens two additional points in the ringing current circuit and reconnects the rear talking leads C2573 and C2575 to the front talking leads and to the line terminals of the hybrid coil 2905. From the above explanation it will be understood that the operation of ringing over the rear end of the link 15 may be repeated as desired by appropriate manipulation of the ring rear key 4040, which key directly controls the two relays R3140 and R3200. Moreover, this key, if desired, may be actuated in accordance with a predetermined code for the purpose of transmitting coded ringing current through the rear end of the link.

Coin collect—front and rear

The operator attending the No. 1 position of the switchboard in handling paystation line toll calls will normally follow the practice of collecting the coins deposited for an initial talking period, before operating the disconnect key 4005 to disconnect the position circuit 18 from the link occupied with the call. If the call is one originating at a paystation in the area served by the central office 10, and the toll charges are to be paid at this station, the collection and refunding of coins deposited at the station must be controlled over the link occupied with a call. For example, if the illustrated link 15 is utilized to extend a call to the operator position circuit 18 from a paystation in the central office area, the operator, in order to collect coins deposited at the calling paystation, may operate the coin collect rear key 4020. When this key is moved to its off-normal position a circuit including the contacts 4021 and the lead C4085 is completed for energizing the split answer relay R3200. At the contacts 4023, a path is prepared for impressing positive booster battery potential upon the upper talking wiper 2401 of the answer switch 16. At the contacts 4022, a path is prepared for impressing ground potential upon the lower talking wiper 2402 of the answer switch 16. The split call relay R3200, in operating, completes both of these paths. More specifically, the path for impressing positive booster battery potential upon the talking wiper 2401 extends from the positive terminal of the booster battery by way of the winding of R4038, the filament of the lamp 4035, the contacts 4023, C4090, the contacts 3205, C2573, the contacts 2562, and the contacts 2441. When this path is completed, a circuit is closed for energizing the relay R4038 in series with the coin collect magnet of the calling paystation and the filament of the lamp 4035. When energized in this circuit, the lamp 4035 is illuminated to indicate that the circuit is closed and the relay R4038 closes its contacts 4039 to energize the common coin control lamp 4126. After the coin collecting operation is completed, the talking wiper 2401 is disconnected from ground in the paystation circuit, whereby the lamp 4035, the relay R4038 and the lamp 4126 are all deenergized to indicate that the coin collecting operation has been completed. Upon receiving this signal the operator handling the call may release the coin collect rear key 4020, thereby to open the established paths for impressing positive booster battery potential and ground potential respectively upon the talking wipers 2401 and 2402 of the answer switch 16. Incident to the release of the key 4020, the split answer relay R3200 is deenergized and restores to reconnect the rear talking leads C2573 and C2575 to the line terminals of the hybrid coil 2905 and the front talking leads C2572 and C2574.

If a connection as set up through the front end of the link, i. e., the call switch 17, is extended to a paystation against which the charges for the call are to be assessed, the operator handling the call must actuate the coin collect front key 4030 in order to effect the operation of the coin collect magnet provided at the called substation. When this key is moved to its off-normal position paths are prepared at the contacts 4032 and 4033 respectively for impressing ground potential and positive booster battery potential upon the two talking wipers of the call switch 17. At the contacts 4031 a circuit including the lead C4082 is

completed for energizing the split call relay R3150. In operating, this relay opens its contacts 3151 and 3154 to disconnect the front talking leads C2574 and C2572 from the rear talking leads and from the line terminals of the hybrid coil 2905. At its contacts 3152 and 3155, the relay R3150 completes the paths for impressing ground potential and positive booster battery potential upon the respective talking wipers of the call switch 17. More specifically, when this relay operates, a circuit including the upper talking conductor of the call switch 17, the contacts 2621 and 2561, C2572, the contacts 3155, C4081, and the contacts 4033 is completed for energizing the coin collect magnet at the called paystation in series with the filament of the lamp 4035 and the winding of the relay R4038. When this circuit is completed, the coin collect magnet of the called paystation operates to collect the deposited coins and the relay R4038 operates to energize the coin control lamp 4126. Following these operations, the circuit is broken at the called paystation, causing the lamp 4035, the relay R4038, and the lamp 4126 to be deenergized in an obvious manner. Thereafter and when the key 4030 is released, the contacts 4033 and 4032 are opened to disconnect the upper and lower talking conductors of the call switch 17 from the booster battery source and ground, respectively. At the contacts 4031 of the key 4030, the split call relay R3150 is deenergized. This relay, in restoring, reconnects the front talking leads C2574 and C2572 to the line terminals of the hybrid coil 2905 and the rear talking leads C2575 and C2573.

Coin refund—front and rear

The manner in which the two coin return keys 4000 and 4010 may be controlled to impress negative booster battery potential and ground potential upon the talking leads extending to the rear and front of the link 15, for example, for the purpose of effecting a coin refund operation at a calling or called paystation against which toll charges are to be assessed, will be clearly apparent from the foregoing explanation. In this regard it will be noted that the coin return rear key 4000 includes contacts 4001 for directly controlling the energization of the split answer relay R3200. This key also includes contacts 4002 and 4003 over which the rear control leads C4089 and C4090 may be respectively connected to ground and to the negative terminal of an available booster battery source. Similarly, the coin return front key 4010 includes contacts 4011 for directly controlling the energization of the split call relay R3150. This key also includes contacts 4012 and 4013 over which the front control leads C4080 and C4081 may respectively be connected to ground and to the negative terminal of the available booster battery source. It will be noted that the path to the negative terminal of the booster battery source commonly extends from the contacts 4003 and 4013 through the filament of the lamp 4034 and the winding of the relay R4036. Accordingly, both of these lamps are energized when a circuit is completed through the contacts of either of the two keys 4000 and 4010 for energizing the coin return magnet of a distant paystation. When energized in such a circuit, the relay R4036 closes its contacts to energize the coin control lamp 4126, and the lamp 4034 is illuminated to indicate the particular coin control operation in progress. The two indicated lamps and the relay R4036 are deenergized when the desired coin

refunding operation is completed at the calling or called paystation.

Split—front and rear

The operator, in handling a call routed to the first position of the switchboard 11 through the link 15 and extended through this link to a called substation, may find it necessary to exclude the called party from the connection in order to hold an uninterrupted conversation with the calling party. This may be accomplished by operating the cut-off front key 4130 to its off-normal position wherein a circuit including the front control lead C4082 is completed for energizing the split call relay R3150. In operating, this relay opens its contacts 3151 and 3154 to disconnect the front talking leads C2574 and C2572 from the rear talking leads C2573 and C2575 and the line terminals of the hybrid coil 2905. Thus the called party is excluded from the conversational circuit established between the calling substation and the first position of the switchboard 11. At its contacts 3152, 3153, 3155 and 3156, the relay R3150 bridges the terminating impedance comprising the resistor 3143 and the condenser 3142 across the front talking leads C2574 and C2572. This impedance simulates the impedance represented by the calling end of the connection as measured in the link 15 and is utilized to maintain the called end of the connection balanced, thereby to prevent any voice current repeaters which may be included in this portion of the connection from singing. When the cut-off front key 4130 is released, the front control lead C4082 is disconnected from ground to deenergize the split call relay R3150. This relay, in restoring, opens its contacts 3152, 3153, 3155 and 3156, to disconnect the terminating impedance from the front talking leads C2574 and C2572. At its contacts 3151 and 3154, the relay R3150 reconnects the front talking leads C2574 and C2572 to the line terminals of the hybrid coil 2905 and the rear talking leads C2575 and C2573.

If the operator handling the call finds it necessary to converse with the called party to the exclusion of the calling party, she may actuate the cut-off rear key 4120. When this key is moved to its off-normal position the rear control lead C4085 is connected to ground to energize the split answer relay R3200. In operating, this relay opens its contacts 3201 and 3204 to disconnect the rear talking leads C2575 and C2573 from the front talking leads and the line terminals of the hybrid coil 2905. Thus the calling party is excluded from the connection. At its contacts 3202, 3203, 3205 and 3206, the relay R3200 connects the terminating impedance comprising the resistor 3143 and the condenser 3142 across the rear talking leads C2575 and C2573, over a path which also includes the contacts 3141 and 3352.

When the cut-off rear key 4120 is released, the rear control lead C4085 is disconnected from ground to deenergize the split answer relay R3200. This relay, upon restoring, closes its contacts 3201 and 3204 to again connect the rear talking leads to the front leads and the line terminals of the hybrid coil 2905. Thus a three-way connection between the calling and called substations and the operator position circuit 18 is reestablished. At its contacts 3202, 3203, 3205 and 3206, the relay R3200 disconnects the terminating impedance 70 from the rear talking leads.

Releasing—front and rear

The operator at the first position of the switchboard 11 in handling the various types of calls 75

that may be routed to the switchboard, and in providing the services required by the calling and called subscribers, may frequently find it necessary to release the calling or called end of a connection as set up through the link 15, for example, without releasing the other end of the connection. This operating feature is particularly useful in the handling of delayed calls wherein the operator may have difficulty in locating either the calling or the called subscriber. If the operator at this position desires to release the rear end of the link 15 and the switches which precede or follow this end of the link, while holding a connection as extended over the front end of the link, i. e., through the call switch 17, she may actuate the release rear key 4060 to its off-normal position wherein a circuit including the contacts 4061 and the control lead C4085 is completed for energizing the split answer relay R3200. In operating, this relay performs the functions described above. At the contacts 4062, a path is prepared for short-circuiting the winding of the sender seize relay R3250 and the lower winding of the change-over relay R2480. At the contacts 4063, a circuit is completed for energizing the error relay R3220, this circuit extending from ground by way of the contacts 2915, C4132, the contacts 4101 and 4063, C4081, and the winding of R3220 to battery.

In operating, the relay R3220 closes its contacts 3221 to short-circuit the sender seize relay R3250 over a path which includes the lead C4092 and the contacts 4062. At its contacts 3221, the relay R3220 also short-circuits the lower winding of the change-over relay R2480 over a path which includes the grounded lead C4092, the contacts 3221, C2579, the contacts 2569, and the contacts 2442' or 2462'. At its contacts 3222, the relay R3220 opens a point in one of the operating circuits for the relay R3430 and opens one of the paths over which the link start lead C2580 may be connected to ground in the position circuit 18. At its contacts 3223, the relay R3220 opens a point in the common portion of the previously traced operating circuits for the start relay R3310 and the sender start relay R3430.

When the above-traced short-circuiting paths are completed, the two relays R2480 and R3250 both restore. In releasing, the relay R3250 disconnects the link start lead C2580 from ground, thereby to deenergize the link start relay R2530. When the two relays R2530 and R2480 restore, the rear end of the link is released in a manner which will be clearly apparent from the preceding explanation. It will be noted, however, that the cut-through relay R2620 is held operated in the link, so that the front end of the connection, i. e., that extending through the call switch 17, is held from the operator position 18. After the rear end of the link 15 has been released, the operator may restore the release rear key 4060 to normal, thereby to cause the deenergization and release of the split answer relay R3200 and the error relay R3220 in an obvious manner. When the key contacts 4062 are opened, the path short-circuiting the winding of the relay R3250 is broken. The latter relay, however, remains in its restored position since the operating circuit therefor is now open at the contacts 2487 of the restored change-over relay R2480. The error relay R3220, upon restoring, opens its contacts 3221 further to interrupt the paths for short-circuiting the winding of the sender seize relay R3250 and the lower winding of the change-over relay R2480. At its contacts 3222, the relay R3220 reprepares the

path for connecting the link start lead C2580 to ground. At its contacts 3223, the relay R3220 prepares the operating circuit for the start relay R3310, this circuit not being held open at the contacts 3231. After the rear end of the link 15 has been released in the manner just described, a new connection may be routed through this end of the link, a delayed call selector and succeeding switches to any desired substation or operator position, in the manner fully explained below.

If the operator desires to release the front end of the link 15 while holding a connection set up through the rear end of the link, she may actuate the release front key 4070 to its off-normal position. When this key is moved off-normal, a circuit including the contacts 4071 and the front control lead C4082 is completed for energizing the split call relay R3150. This relay, in operating, cuts off the connection extending to the front of the link, i. e., through the call switch 17, and otherwise performs the functions described above. At the contacts 4072, a multiple circuit including the front control lead C4084 is completed for energizing the upper winding of the relay R3230. At these contacts, a path is also completed for short-circuiting the upper winding of the cut-through relay R2620, this path extending from ground by way of the contacts 4072, C4084, C2577, the contacts 2567, the upper winding of R2620 and the contacts 2628 back to ground. When this path is completed, the relay R2620 is de-energized and restores. In releasing, the relay R2620 opens its contacts 2629, thereby to disconnect the control conductor of the trunk extending to the call switch 17 from ground and thus effect the release of this switch and the succeeding switches in the usual manner. At its contacts 2628, the relay R2620 opens a point in its own locking circuit and interrupts the initially completed circuit for energizing the relay R3230. At its remaining contacts, the relay R2620 prepares the link circuit for the extension of a second connection through the call switch 17 to a desired destination. In this regard it will be understood that the connect relays R2630 and R2560 remain operated in the link following the release of the cut-through relay R2620.

When the release front key 4070 is released, the relays R3150 and R3230 are deenergized and restore. In releasing, the relay R3230 closes its contacts 3231 to complete the previously traced operating circuit for the sender start relay R3430. The latter relay, in operating, effects the seizure of the control circuit 20 and the register sender 21, and the operation of the start send relay R2650 in the exact manner previously explained. Accordingly, the operator may extend a new connection through the call switch 17 by the simple expedient of keying up the directory number designating the desired destination on the key set 22 and then operating the disconnect key of the key set, all in the manner previously described.

Automatic answer cut-out

As pointed out in the preceding explanation, calls are automatically extended to the No. 1 position of the operator switchboard 11 under the control of the link distributor 19 and the common start circuit 12, no key operations being required on the part of the operator attending this position to bring the calls in for answering. It will also be recalled that the operator attending this position of the switchboard is in each case informed that a call is being routed to her position for answering shortly before the call is actually

routed to the position by the transmission of a zip-zip tone to the receiver 2901. If desired, the operator at this position may block the automatic answer facilities by operating the automatic call answer cut-out key 2908 and accept the calls at her leisure by operating the accept call key 2907 each time she is ready to receive and handle another call. The automatic call cut-out key is of the well-known locking type, such that when once operated to its off-normal position it remains in that position until manually restored to normal. When this key is actuated to its off-normal position a circuit including the contacts 2912 and 2921 is completed for energizing the cut-out relay R2930. In operating, the relay R2930 opens its contacts 2931 to interrupt the previously traced operating circuit for the start relay R3310. The relay R3310, upon restoring, closes its contacts 3313 to connect the position guard lead C3962 to ground, whereby the position circuit 18 is marked as busy in the position distributor 13. Thus the distributor 13 is prevented from allotting the No. 1 position of the switchboard to receive calls. At its contacts 3314, the relay R3310 disconnects the start lead C3963 from ground in the position circuit 18. At its contacts 3311, the relay R3310 opens a point in the previously traced operating circuit for the position start relay R3210. From an inspection of the circuits involved, it will be understood that so long as the cut-out relay R2930 remains in its operated position, the start relay R3310 cannot be energized for the purpose of marking the position circuit 18 as idle in the position distributor 13. If, during an interval when the automatic call cut-out key 2908 is operated, the operator handling calls at the first position of the switchboard desires to receive a call, the accept call key 2907 is momentarily operated to its off-normal position to complete a circuit through the contacts 2913 for energizing the accept call relay R2920. This relay, in operating, closes its contacts 2922 to prepare a locking circuit for itself. At its contacts 2921, the relay R2920 deenergizes the cut-out relay R2930. The latter relay, in releasing, closes its contacts 2931 to energize the start relay R3310 over the previously traced circuit. In operating, this start relay closes its contacts 3312 to complete the prepared locking circuit for the accept call relay R2920, this circuit extending from ground by way of the contacts 3312, 3257 and 2922, and the winding of R2920 to battery. At its contacts 3313, the relay R3310 disconnects the position guard lead C3962 from ground, thereby to mark the position circuit 18 as idle in the position distributor 13. At its contacts 3314, the relay R3310 connects the start lead C3963 to ground. At its contacts 3311, the relay R3310 prepares the operating circuit for the position start relay R3210. Following the operation of the start relay R3310, and when the position circuit 18 is allotted for use under the control of the position distributor 13, the common start circuit 12 is free to function in the manner previously described to route a call to the position circuit 18 through one of the links associated therewith. The manner in which these various operations are performed is exactly the same as described above, and from this description it will be recalled that the sender seize relay R3250 is energized incident to the operation of an associated link to extend the call to the position circuit 18. This relay, in operating, opens its contacts 3256 to deenergize the start relay R3310 and, at its contacts 3257, opens the established locking circuit for the accept call relay R2920.

In releasing, the relay R2920 closes its contacts 2921 to recomplete the operating circuit for the cut-out relay R2930 and, at its contacts 2922, opens another point in its own locking circuit. The cut-out relay R2930, in reoperating, reopens its contacts 2931 to prevent the start relay R3310 from being energized when the position circuit 18 is subsequently disconnected from the link occupied with the call. Thus before another call can be routed to the first position of the switchboard, it is necessary for the operator attending this position momentarily to operate the accept call key 2907 to cause the reoperation of the accept call relay R2920, the deenergization of the cut-out relay R2930, and the operation of the start relay R3310.

In order to recondition the operator position circuit 18 to again receive calls on an automatic basis, i. e., without operation of the accept call key 2907, the operator attending the No. 1 position of the switchboard must restore the automatic call answer cut-out key 2908 to its normal position, thereby to deenergize the cut-out relay R2930. With this relay in its restored position, the operating circuit for the start relay R3310 is maintained through the contacts 2931.

Emergency start

The operator at any one of the operator positions of the switchboard 11 may cause the answer switch of an allotted one of the associated links to seize a calling trunk circuit through its outlet contacts without regard to the operation of the position distributor 13. For example, if the link 15 is assigned by the link distributor 19 to route a call to the operator position circuit 18, the operator attending the first position of the switchboard 11 may force the answer switch 16 to search for a calling trunk circuit by operating the emergency start key 4110 to its off-normal position. In response to this operation, a circuit is completed for energizing the position start relay R3210, this circuit extending from ground by way of the contacts 2915, C4132, the contacts 4112 of the key 4110, C4131, the contacts 3032 and the winding of R3210 to battery. In operating, the start relay R3210 causes the answer switch 16 to search for a calling trunk circuit in the exact manner previously explained. In the present case the vertical movement of the wipers 2401 to 2409, inclusive, will be arrested when these wipers are positioned opposite the first level of bank contacts before which a call is waiting. The rotary movement of these wipers is arrested and the switch-through operation of the answer switch 16 completed when the wipers are positioned on the set of contacts in the associated contact field at which the first calling trunk circuit is terminated. The particular type of call which is extended to the operator position circuit 18 in response to the forced operation of the start relay R3210 will, of course, depend upon the setting of the change call relays R2710 and R2720 in the common start circuit 12, for reasons previously explained. Incident to the seizure of the link 15 through the forced operation of the position start relay R3210, the connect relays R2630 and R2560 are energized and locked up; the link guard lead C3842 is connected to ground through the contacts 2463' or 2443', thereby to mark the link 15 as busy in the link distributor 19; and the sender seize relay R3250 is energized in the position circuit 18 to deenergize the start relay R3310 and thus mark the position circuit as busy in the position distributor 13. Also incident to

the operation of the sender seize relay R3250, the sender control circuit 20 and the register sender 21 are seized, and the start send relay R2650 is operated, all in the manner previously described. After the call has been extended to the position circuit 18 the operator attending the No. 1 position of the switchboard may release the emergency start key 4110 to deenergize the position start relay R3210. From this point on the call may be handled in the exact manner explained above.

Position transfer

It is noted that if an operator at any one of the positions of the switchboard 11 finds it necessary to vacate her position at a time when a call is established through one of the links associated with her position, she may transfer the call to the succeeding operator position for supervision. For example, if the operator attending the No. 1 position of the switchboard desires to vacate her position during an interval when a connection is established through the illustrated link 15, for example, she may transfer the call to the second operator position for supervision by operating the transfer key 4015 to its off-normal position, wherein a circuit including the lead C4088 is completed for energizing the position transfer relay R3100. In operating, the relay R3100 opens its contacts 3105' to deenergize the all-links-busy relay R3020. At its contacts 3104', the relay R3100 opens the previously traced operating circuit for the start relay R3310, causing the latter relay to release if operated. It will be noted that with the two relays R3020 and R3310 restored, the position circuit 18 is marked as busy in the position distributor 13 and operation of the link distributor 19 associated with this position circuit is arrested. At its contacts 3101 to 3104, inclusive, the relay R3100 disconnects the two monitor leads C2562 and C2561 as well as the front and rear talking leads from the line terminals of the repeating coil 2906 and connects these leads to the monitor leads C3170 and C3171 of the position circuit serving the second position of the switchboard 11. At its contacts 3105, the relay R3100 prepares a circuit including the conductor C3172 for energizing the relay R3230 as provided in the position circuit 50 serving the adjacent second position. At its contacts 3106, the relay R3100 opens a point in the previously traced operating circuit for the connect relay R2630 of an assigned link. At its contacts 3107 and 3108, the relay R3100 prepares a circuit for controlling the connect relay R2630 of the link 15 from the operator position circuit serving the second operator position. At its contacts 3109 and 3101', the relay R3100 disconnects the control lead C2563 from the monitor relay R3000, and prepares a circuit including the lead C3174 for energizing the monitor relay of the position circuit at the adjacent position under the control of the monitor key 2540. At its contacts 3102' and 3103', the relay R3100 opens a point in the operating circuit for the switching relay R3010 of the illustrated position circuit 18, and prepares a circuit including the lead C3175 for energizing the corresponding switching relay as provided in the position circuit serving the No. 2 operator position.

With the position transfer relay R3100 operated, the operator attending the adjacent second position may actuate the monitor key 2540 of the link 15 to set up a monitoring connection to her headset which includes the monitor leads C2562

and C2561, the contacts 3102 and 3104, and the monitor leads C3170 and C3171 extending to her own position circuit. In this case, the monitor relay of the position circuit serving the second operator position is energized over a circuit which includes the grounded conductor C2563, the contacts 3101', and the conductor C3174.

If the operator at the adjacent second position desires to enter the connection established through the link 15, she may actuate the talk key 2550 to its off-normal position and thus energize the connect relays R2630 and R2560, the relay R3040, and the relays R3010, R3050 and R3230 as provided in the position circuit serving the second operator position. In this case the connect relay R2630 is energized over a circuit which includes the lead C3173 which is connected to ground through the break contacts of the switching relay R3010 and the make contacts of the battery feed relay R2910 as provided in the position circuit serving the adjacent position. Upon operating, the connect relay R2630 locks to ground through the winding of the switching relay R3010 as provided in the position circuit of the adjacent position over a path which includes the lead C2576, the contacts 3042 and 3103', and the lead C3175 extending to the position circuit serving the adjacent operator position. The switching relay of the position circuit serving the adjacent operator position, in operating, connects the line terminals of the hybrid coil in that circuit to the front and rear talking leads of the illustrated position circuit over paths which respectively include the contacts 3102 and 3104. The relay R3040 of the position circuit 18, upon operating in response to operation of the talk key 2550, closes its contacts 3041 to complete a circuit including the contacts 3105 and the lead C3172 for energizing the relay R3230 as provided in the position circuit of the adjacent operator position. The purpose of operating this relay is to deenergize the start relay R3310 as provided in the position circuit of the adjacent position, whereby this position circuit will be marked as busy in the position distributor 13.

The operator at the adjacent position, in order to disconnect her position circuit from the link 15 following operation of the talk key 2550 in the manner just explained, may operate the disconnect key 4005 for the purpose of energizing the disconnect relay R3030. This relay, in operating, deenergizes the relay R3040. The latter relay, upon restoring, opens its contacts 3041 to deenergize the relay R3230 as provided in the position circuit of the adjacent position. At its contacts 3042, the relay R3040 opens the established circuit over which the connect relay R2630 is locked energized in series with the switching relay R3010 as provided in the position circuit of the adjacent operator position. The connect relay R2630 and its associated relay R2560, upon restoring in the link 15, disconnect the talking leads C3170 and C3171 extending to the position circuit of the adjacent operator position from the talking circuit established through the link 15. The operator at the adjacent position may also release the connection as set up through the link 15 by actuating the release key 2556. In response to this operation the link 15 and the switches on either side thereof are released in the exact manner explained above.

When the operator returns to the No. 1 position of the switchboard, she may restore the position transfer key 4015 to normal, thereby to deenergize the position transfer relay R3100. This

relay, in releasing, recloses its contacts 3104' and 3105' to recomplete the operating circuits for the start relay R3310 and the all-links-busy relay R3020. At its remaining contacts the relay R3100 disconnects the illustrated position circuit 18 from the position circuit of the No. 2 operator position and re-establishes the circuit connections over which the links associated with the No. 1 position of the switchboard may normally be controlled. When the two relays R3310 and R3020 are reoperated, one of the links associated with the No. 1 position of the switchboard is automatically selected for use and this position is marked as idle in the position distributor 13.

Seizing the common register senders

As previously indicated, each position of the operator switchboard is equipped with an individual register sender which is normally used in extending calls from the associated switchboard position. Thus the register sender comprising the digit registers 21B and the impulse sender 21A is individually associated with the illustrated No. 1 position of the switchboard and normally is used in handling all calls routed to this switchboard position. Each of the positions of the switchboard also has access to two common register senders 51 and 52, which may be used in lieu of the register sender individual thereto if for any reason the individual sender is not operating properly. So long as the two register senders 51 and 52 are not in use, the signal lamps 4123 and 4124 individually associated therewith and provided at each of the operator positions of the switchboard 11 are deenergized.

If the operator at the No. 1 position of the switchboard finds it necessary to use one of the common register senders in lieu of the register sender 21, she may actuate the common sender key 4140 in order operatively to associate the register sender 51 with the sender control circuit 20. When this key, which is of the locking type, is operated to its off-normal position, a circuit is completed for energizing the relay R3730. This circuit may be traced as extending from ground through the contacts of the common sender key 4140 by way of C4136, the winding of R3730, the contacts 3734, the contact 3732 and the intervening chain-connected contacts controlled by the sender relays associated with the register sender 51 and individual to the other operator positions of the switchboard, and the resistor 3736 to battery. In operating, the relay R3730 closes its contacts 3731 to connect the signal lead C4138 to ground and thus energize the signal lamps 4123 as provided at the different positions of the switchboard 11. Thus an indication is produced at each position of the switchboard that the common register sender 51 is busy. At its preliminary make contacts 3733, the relay R3730 completes an obvious locking circuit for itself. After completing this circuit, the relay R3730 opens its contacts 3732 and 3734 to interrupt its own operating circuit and a point in the operating circuits for the sender relays individual to the other positions of the switchboard and associated with the register sender 51. Thus with the relay R3730 operated the register sender 51 cannot be seized from any of the other positions of the switchboard. At its contacts 3735, the relay R3730 completes an obvious circuit for energizing the transfer relay R3710.

In operating, the transfer relay R3710 opens its contacts 3711 and 3712 and closes its contacts 3711' and 3712', thereby to disconnect the pulsing

leads of the sender control circuit 20 from the pulsing leads E1 and F1 extending to the register sender 21 and to connect the pulsing leads of the sender control circuit to the pulsing leads E2 and F2 extending to the register sender 51. At its contacts 3713 to 3716, inclusive, the relay R3710 disconnects the four code leads A, B, C and D of the key set 22 from the four code leads A1, B1, C1 and D1 extending to the register sender 21. At its contacts 3713' to 3716', the relay R3710 connects the four key set code leads to the four code leads A2, B2, C2 and D2 extending to the register sender 51. At its contacts 3717 and 3717', the relay R3710 disconnects the E. C. 1 lead of the sender control circuit from the E. C. 1 lead extending to the register sender 21, and connects it to the E. C. 2 lead extending to the register sender 51, thereby to prepare a circuit over which the sender stop relay R4310 of the register sender 51 may be controlled. At its contacts 3718 and 3718', the relay R3710 disconnects the control lead of the sender control circuit 20 from the sender control lead T1 extending to the register sender 21, and connects this lead to the sender control lead T2 extending to the register sender 51, thereby to prepare circuits over which the start relay of the register sender 51 may be controlled from the sender control circuit 20 as well as circuits over which the sender supervisory relay R3640 and the release relay R3610 of the sender control circuit 20 may be controlled over the register sender 51. From the above explanation it will be understood that after the transfer relay R3710 operates, the register sender 51 may be controlled by the key set 22 and the sender control circuit 20 to perform all of the functions previously described with reference to the operation of the register sender 21 in the extension of calls from the No. 1 position of the switchboard 11.

When the operator attending the first position of the switchboard no longer requires the use of the common register sender 51, she may disconnect this sender from the key set 22 and the sender control circuit 20 by restoring the common sender key 4140 to normal. In response to this operation, the relays R3730 and R3710 are sequentially released in an obvious manner. The relay R3730, upon restoring, opens its contacts 3731 to disconnect the signal lead C4138 from ground and thus deenergize the sender signal lamps 4123 as provided at the different positions of the operator switchboard. Thus an indication is produced that the common register sender 51 is idle and may be seized from any one of these positions. In releasing, the relay R3730 also closes its contacts 3732 to reprepare the operating circuits for the sender relays associated with the register sender 51 and individual to the various positions of the switchboard 11. The transfer relay R3710, upon restoring, opens its contacts 3711' to 3718', inclusive, thereby to disconnect the key set 22 and the sender control circuit 20 from the common register sender 51. At its break contacts 3711 to 3718, the relay R3710 reconnects the key set 22 and the control circuit 20 to the register sender 21.

The manner in which the second common register sender 52 may be operatively associated with the key set 22 and the sender control circuit 20 under the control of the operator attending the first position of the switchboard will be readily apparent from the above explanation. In this regard it will be understood that when the common sender key 4150 is operated, the relay R3740

is energized to guard the register sender 52 against seizure from any of the other operator positions. In operating, this relay also closes its contacts 3745 to energize the transfer relay R3720. 5 At its contacts 3741, the relay R3740 connects the signal lead C4139 to ground, thereby to energize the signal lamps 4124 as provided at the different operator positions. Thus an indication is produced at each position of the switchboard which 10 identifies the common register sender 52 as busy. The transfer relay R3720, in operating, opens its contacts 3721 to 3728, inclusive, to disconnect the key set 22 and the sender control circuit 20 from the register sender 21. At its make contacts 3721' to 3728', the relay R3720 connects the sender control circuit 20 and the key set 22 to the common register sender 52. In order to release this sender and to re-establish the connections between the sender control circuit 20, the key set 22 and the register sender 21, the operator may restore 15 the common sender key 4150 to normal, thereby to cause the sequential release of the two relays R3740 and R3720 in an obvious manner. Upon restoring, the relay R3740 reprepares the operating circuits for the sender relays associated with the common sender 52 and individual to the various operator positions, thereby to render this sender accessible to the different positions. In 20 releasing, the relay R3740 also disconnects the signal leads C4139 from ground, whereby the signal lamps 4124 respectively provided at the different positions of the switchboard are deenergized. The transfer relay R3720, upon restoring, disconnects the key set 22 and the sender control 25 circuit 20 from the common register 52 and reconnects these two control units to the register sender 21.

Dialing over the rear end of the link

40 In the normal use of the switchboard 11, the calls are routed to the switchboard through the rear ends of the operator position links and are extended over the front ends of these links to their destination. This, of course, means that 45 normally all dialing takes place over the front ends of the links. Under certain circumstances, however, it is necessary to dial over the rear ends of the links. For example, in the handling of delayed calls it is frequently expedient for the 50 operators to extend connections through the answer switches of the links.

In considering this type of service it may be assumed that the operator attending the No. 1 position of the switchboard 11 is handling a call 55 which may be most expeditiously disposed of by dialing over the rear end of one of the links associated with this operator position. It may be assumed further that the link 15 is either occupied with the call in question or is set up for use by the link distributor 19 at the time the operator requires the use of a link to handle the call. In this regard it will be noted from the following explanation that if the call is initiated at the first position of the switchboard, the operator has no facilities for selecting the link to be used in handling the call. On the contrary, she is forced to use the particular link selected 60 for use by the link distributor 19. To dial on the rear end of the link 15, the operator actuates the dial rear key 4100 to its off-normal position. In response to this operation a circuit including the grounded control lead C4132, the contacts 4102, the emergency start lead C4131, and the contacts 3032 is completed for energizing the position start relay R3210. At the contacts 75

a path including the grounded lead C4132 and the marking lead C4133 is completed for impressing marking ground potential upon the first contact of the level marking contact set 2410 for the purpose of arresting the vertical movement of the answer switch wipers after these wipers are elevated to a position opposite the first level of contacts, wherein the trunks extending to the delayed selectors are terminated. At the contacts 4101, a point is opened in the operating circuit for the error relay R3220. At the contacts 4104, a circuit is completed for energizing the dial rear relay R3340, this circuit extending from the grounded lead C4132 by way of the contacts 4104, C4134, the contacts 3323, and the winding of R3340 to battery. At the contacts 4105, a path is prepared for impressing negative battery potential upon the rear talking lead C2575 for a purpose to be described hereinafter.

The relay R3340, upon operating, closes its contacts 3341 to prepare a locking circuit for itself. At its contacts 3342, the relay R3340 prepares an alternative circuit for energizing the switching relay R3010 in series with the lower winding of the connect relay R2630. At its contacts 3343, the relay R3340 prepares an alternative path for short-circuiting the winding of the relay R3250 and the lower winding of the change-over relay R2480. At its contacts 3344, the relay R3340 opens a point in the operating circuit for the tone relay R3110. At its contacts 3345, the relay R3340 prepares a locking circuit for the relay R3240 and completes an obvious circuit for energizing the split answer relay R3200. At its contacts 3346, the relay R3340 completes an obvious circuit for energizing the dial rear relay R3350. At its contacts 3348, the relay R3340 opens a point in the previously traced operating circuit for the sender start relay R3430. At its contacts 3347, the relay R3340 prepares an alternative operating circuit for the sender start relay. At its contacts 3349, the relay R3340 opens the operating circuit for the start relay R3310, whereby the latter relay, if operated, restores to mark the position circuit 18 as busy in the position distributor 13. At its contacts 3342', the relay R3340 opens a point in the previously traced circuit for energizing the rear supervisory relay R3260. At its contacts 3341', the relay R3340 prepares a circuit including the E. C. wiper 2408 of the answer switch 16 over which the supervisory relay R3530 of the sender control circuit 20 may be controlled.

The relay R3350, upon operating, closes its contacts 3351 to prepare one of the operating circuits for the blocked sender relay R2610 and, at its contacts 3352, opens a point in the previously traced path for bridging the terminating impedance 3142, 3143 across the rear talking leads C2573 and C2575. At its contacts 3353 and 3354, the relay R3350 prepares a circuit for transmitting impulses from the impulse sender 21A over the rear talking leads C2573 and C2575 to a delayed call selector seized through the answer switch 16. At its contacts 3355, the relay R3350 prepares the operating circuit for the cut-in relay R3320. At its contacts 3356, the relay R3350 prepares the operating circuit for the dial rear relay R3420 of the sender control circuit 20.

The split answer relay R3200, upon operating, closes its contacts 3205 and 3202 to connect the rear talking leads C2573 and C2575 through the contacts 3354 and 3353, respectively, to the pulsing leads C2661 and C2662 of the sender control circuit 20.

The start relay R3210, upon operating, closes its contacts 3212 to energize the relay R3040 and, at its contacts 3211, completes the previously traced distributor controlled operating circuit for the connect relay R2630. At its contacts 3213, the relay R3210 prepares the operating circuit for the link start relay R2530. At its contacts 3213, the relay R3210 also completes the above-mentioned alternative operating circuit for the sender start relay R3430, this circuit extending from ground by way of the contacts 3213, 3222, 3347 and 3402, and the winding of R3430 to battery.

When the sender start relay R3430 operates, it functions to cause the sequential operation of the relays R3400, R3700, R3620 and R3640, and to cause the seizure of the impulse sender 21A and the digit registers 21B in the exact manner previously described. In this case, the connect relay R3400 in closing its contacts 3401 and 3402 and the sender connect relay R3700 in closing its contacts 3701 and 3702, connect the pulsing leads E1 and F1 of the impulse sender 21A to the rear talking leads C2573 and C2575. At its contacts 3403, the relay R3400 also prepares the operating circuit for the cut-in relay R3320. At its contacts 3404, the relay R3400 further prepares the circuit for controlling the supervisory relay R3530 over the rear end of the link 15. At its contacts 3407, the relay R3400 completes the prepared operating circuit for the dial rear relay R3420. The remaining functions performed by the connect relay R3400 are the same as previously described.

The dial rear relay R3420, upon operating, opens its contacts 3421 to interrupt the operating circuit for the start send relay R2650 and thus cause this relay to restore if operated. With the start send relay of the link 15 in its restored position, the sender control leads C2661 to C2668, inclusive, are disconnected from the link circuit equipment so that no impulses can be transmitted to the front end of the link during the subsequent operation of the impulse sender 21A. At its contacts 3422, the relay R3420 prepares the operating circuit for the dial rear lock relay R3240. At its contacts 3423, the relay R3420 locks to ground through the contacts 3408.

As indicated above, the relays R3040 and R2630 are energized in response to operation of the position start relay R3210. The operation of the relay R3040 is without effect. The connect relay R2630, upon operating, locks up in a circuit which includes its contacts 2631, C2576, the contacts 3342, and the winding of the switching relay R3010. When this locking circuit is completed, the relay R3010 operates to connect the front talking leads C2572 and C2574 to the line terminals of the hybrid coil 2905, and to close the operating circuit for the relay R3050, all in the manner previously described. The relay R3050, in operating, opens its contacts 3051 to disconnect the lead C3214 from ground and thus prevent the energization of the start relay in a newly selected link associated with the first position of the switchboard.

In operating, the relay R2630 also initiates the operation of the answer switch 16 in the exact manner previously explained. From this explanation it will be recalled that the connect relay R2560 and the start relay R3530 are sequentially operated in response to operation of the connect relay R2630. It will also be recalled that vertical movement of the answer switch wipers 2401 to 2409, inclusive, is initiated in response to operation of the start relay R2530. In the pres-

ent case, the first level of contacts in the contact bank of the answer switch 16 is marked as a calling level through the application of ground potential to the marking lead C4133 terminating in the first contact of the level marking contact set 2410. Accordingly, the vertical movement of the answer switch wipers is arrested and rotary movement thereof is initiated after these wipers are elevated to a position opposite the first level of bank contacts. More specifically, the change-over relay R2480 is, in the case under consideration, energized over a circuit which includes the grounded marking lead C4133, the level test wiper 2489, the upper winding of R2480, the contacts 2515 and 2688, and the winding of the step relay R2470.

During the rotary movement of the wipers 2401 to 2408, inclusive, only those trunks which extend to delayed call selectors are tested. In this regard it is again noted that both the inter-position trunk circuits and the trunks extending to the delayed call selectors are terminated in the first level of bank contacts of each of the answer switches associated with the first two positions of the switchboard, i. e., those positions which are arranged to handle inter-position calls. The inter-position trunk circuits are, however, only marked for seizure in the bank contacts of the answer switches when occupied with calls. These trunk circuits are not terminated in the bank contacts of the answer switches associated with the other positions of the switchboard. It is pointed out, moreover, that the marking relay in each of the inter-position trunk circuits is arranged to be energized in series with the start relay R3210 of the position circuit 18 or the corresponding start relay of the position circuit serving the second operator position of the switchboard. Accordingly, if one of the inter-position trunk circuits receives an incoming call an instant before the dial rear key 4100 is operated, the marking relay thereof is short-circuited over a ground path which includes the grounded lead C4132, the contacts 4102, the emergency start lead C4131, and the contacts 3956 when the dial rear key is operated to its off-normal position. Accordingly, the marking relay of the inter-position trunk circuit occupied with the call is deenergized and releases to open the marking path over which the rotary position of the trunk circuit termination is established in the first level of bank contacts of each of the answer switches serving the first and second operator positions. It will thus be understood that after the dial rear key 4100 is operated, the answer switch 16 can only function to search for an idle one of the delayed call selectors to which it has access.

Assuming that the delayed call selector 47 is the first idle selector of this type accessible to the answer switch 16, the test relay R2430 is operated to arrest the rotary movement of the answer switch wipers when these wipers are positioned to engage the contacts terminating the conductors of the trunk 47d. In operating, this test relay causes a connection to be established between the delayed call selector 47 and the operator position circuit 18 in the exact manner previously explained. In this regard it will be understood that the delayed call selector 47, when seized through the outlet contacts of the answer switch 16, is conditioned to respond to switch directing impulses in the usual manner, and is marked against seizure in each of the other answer switches to which it is accessible.

When the wipers of the answer switch 16 are positioned opposite the first level of bank contacts associated therewith in the manner just explained, the normal post springs 2419 are opened and the normal post springs 2420 are closed. At the latter set of contact springs, a circuit including the E. C. wiper 2408, the contacts 2531', and the rear supervisory lead C2569 is prepared for controlling the supervisory relay R3530 during the dialing operation and for controlling the rear supervisory relay R3280 after the dialing operation is completed. These circuits are further prepared at the contacts 2441' when the switching relay R2440 operates in response to operation of the test relay R2430. In operating, the switching relay R2440 also closes its contacts 2442' to complete the previously traced operating circuit for the sender seize relay R3250. In operating, the sender seize relay R3250 connects the link 20 start lead C2580 to ground through its contacts 3252 and, at its contacts 3251, further prepares the locking circuit for the dial rear relay R3340. The remaining circuit control operations performed by the relay R3250 are without effect.

Following the relay operations just described, the pulsing leads E1 and F1 extending to the impulse sender 21A are connected to the talking leads of the delayed call selector 47 over a channel which extends through the sender control circuit 20, the operator position circuit 18, and the answer switch 16. More specifically, one side of this channel extends from the pulsing lead E1 by way of the contacts 3721, 3711, 3701 and 3401, C2662, the contacts 3353 and 3202, C2575, the contacts 2565 and 2442, and the wiper 2402 to the talking lead 47b of the trunk 47d which extends to the selector 47. The other side of this channel extends from the pulsing lead F1 by way of the contacts 3722, 3712, 3702, 3613 and 3402, C2661, the contacts 3354 and 3205, C2573, the contacts 2562 and 2441, and the wiper 2401 to the opposite talking lead 47a of the trunk 47d. Moreover, the previously mentioned circuit for controlling the supervisory relay R3530 over the E. C. wiper 2408 and the E. C. lead 47e of the trunk extending to the delayed call selector 47 is also established, this circuit extending from the conductor 47e by way of the wiper 2408, the contacts 2441', the normal post springs 2420, the contacts 2531', C2569, the contacts 3341', C2663, the contacts 3404, the winding of R3530, and the contacts 3621.

The operator initiating the delayed call, upon observing that the sender pilot lamp 4125 is energized, may key up the digits of the directory number designating the desired substation or operator position on the key set 22. The impulse sending equipment comprising the digit registers 21B and the impulse sender 21A responds to the operation 55 of the digit keys in the key set 22 to transmit corresponding impulse digits over the above-traced pulsing channel to and through the delayed call selector 47, in a manner which will be clearly apparent from the preceding explanation. The delayed call selector 47 responds to the impulses of the first transmitted digit by operating to extend the connection to a succeeding switching stage, such, for example, as the selector 55, in the usual manner. If the connection is extended to the switching stage comprising the translating selector 55, the second and succeeding digits are routed through a register selector 56 to an idle register sender 57, where they are registered and are then revertively transmitted to

the revertive pulse switches of a succeeding switch train such, for example, as the switch train 58, for the purpose of extending the call to its destination, such, for example, as the substation C. Alternatively, the call may be extended through the outlet contacts of the delayed call selector 47 to the inter-toll dial train and through this train to one of the distant offices, in the manner explained below.

After the digits of the directory number designating the destination of the call are keyed up on the key set 22, the operator handling the call may actuate the disconnect key of this key set to energize the sender disconnect relay R3630, whereby the sender control circuit 20, the impulse sender 21A and the digit registers 21B are conditioned to be released under the control of the release relay R3610 after all of the registered digits have been transmitted by the sender 21A. When the disconnect lead C3644 is connected to ground through the contacts of the disconnect key, the dial rear lock relay R3240 is energized in a circuit which includes this lead and the contacts 3707 and 3422. In operating, the relay R3630 also deenergizes the sender connect relay R3700 and the sender supervisory relay R3640, whereby the key set 22 is disconnected from the register sender 21. At its contacts 3635, the relay R3630 also completes a locking circuit for the dial rear lock relay R3240, this circuit extending from ground by way of the contacts 3622, 3635 and 3422, and the upper winding of R3240 to battery.

In operating, the relay R3240 locks to ground through the contacts 3242 and 3345, and closes its contacts 3241 to complete the prepared locking circuit for the dial rear relay R3360, the latter circuit extending from ground by way of the contacts 3241, 3251, 3321 and 3341, and the winding of R3340 to battery. After all of the digits registered in the registers 21B have been transmitted by the impulse sender 21A, the release relay R3610 is energized and operates to connect the relay R3600 to one side of the connection extending to the last switch of the established switch train. In operating, the relay R3610 also functions to deenergize the hold relay R3620. At its contacts 3611, the relay R3610 also prepares the operating circuit for the cut-in relay R3320.

As previously indicated, the relay R3600 may or may not be momentarily energized in response to the operation of the release relay R3610, depending upon the destination of the call. Assuming that the relay R3600 is not energized the hold relay R3620 releases to deenergize the sender disconnect relay and to open the operating circuit for the dial rear lock relay R3240 shortly following the operation of the release relay R3610. The sender disconnect relay, in restoring, initiates the release of the sender control circuit 20, the impulse sender 21A, and the digit registers 21B in the exact manner previously explained. In this regard, it will be noted that the relays R3610, R3400 and R3420 are sequentially released in the order named in response to the release of the disconnect relay R3630. The connect relay R3400, upon restoring, disconnects the sender control circuit 20 from the position circuit 18. In releasing, the sender disconnect relay R3630 also closes its contacts 3634 to complete the operating circuit for the cut-in relay R3320, this circuit extending from ground by way of the contacts 3634, 2611, 3601

and 3403, C2665, the contacts 3355, and the winding of R3320 to battery.

- In operating, the relay R3320 locks to the grounded lead C4134 through its contacts 3322. 5 At its contacts 3324, the relay R3320 also locks to the grounded cut-in lead C2665. At its contacts 3323 and 3321, the relay R3320 opens the operating and locking circuits for the dial rear relay R3340, causing the latter relay to restore. 10 At its contacts 3325, the relay R3320 opens a point in the initially traced operating circuit for the sender start relay R3430. 15 The relay R3340, upon restoring, opens its contacts 3342 to interrupt one of the established multiple circuits for energizing the switching relay R3010 in series with the lower winding of the connect relay R2630. At its contacts 3341, the relay R3340 opens another point in its own locking circuit. At its contacts 3344, the relay R3340 20 reprepares the operating circuit for the tone relay R3110. At its contacts 3345, the relay R3340 deenergizes the split answer relay R3200 and the dial rear lock relay R3240. The release of the latter relay is without effect. At its contacts 25 3346, the relay R3340 deenergizes the associated dial rear relay R3350. At its contacts 3347, the relay R3340 opens a point in the operating and locking circuits for the sender start relay R3430, thereby to prevent the latter relay from reoperating after the connect relay R3400 restores to 30 reprepare its operating circuit. At its contacts 3348, the relay R3340 reprepares the initially traced operating and locking circuits for the sender start relay R3430. At its contacts 3349, 35 the relay R3340 reprepares the operating circuit for the start relay R3310. At its contacts 3341, the relay R3340 opens a point in the circuit for controlling the supervisory relay R3530 over the rear end of the link 15. At its contacts 3342, 40 the relay R3340 reprepares the operating circuit for the rear supervisory relay R3260.

The relay R3350, upon restoring, opens its contacts 3353 and 3354 to disconnect the rear talking leads of the position circuit from the pulsing 45 leads C2661 and C2662 of the sender control circuit 20. At its contacts 3352, the relay R3350 reprepares the previously traced path for bridging the terminating impedance 3142, 3143 across the rear talking leads C2573 and C2575. At its contacts 3351, the relay R3350 opens a point in one of the operating circuits for the blocked 50 sender relay R2610. At its contacts 3355, the relay R3350 opens a point in the operating circuit for the cut-in relay R3320. At its contacts 3356, the relay R3350 opens a point in the operating circuit for the dial rear relay R3420.

The split answer relay R3200, in releasing, closes its contacts 3201 and 3204 to connect the line terminals of the hybrid coil 2905 to the rear 60 talking leads C2573 and C2575, thereby to establish a talking circuit over which the operator handling the call may converse with the called subscriber or operator when the call is answered. In this regard it is pointed out that ground potential is applied to the E. C. wiper 2408 in the last switch of the train when the call is extended to the called line or trunk. When this wiper is connected to ground, the relay R3260 is energized in a circuit which extends from the 65 grounded wiper by way of the contacts 2441, the normal post springs 2420, the contacts 2531', C2569, the contacts 3342', and the winding of R3260 to battery. In operating, the rear supervisory relay R3260 closes its contacts 3262 to 70 energize the winding of the relay R3300 in parallel.

lel with the resistor 4106 and in series with the resistor 3283. The current flow through the winding of the relay R3300 as included in this series parallel circuit is insufficient to cause the relay to operate. At its contacts 3261, the relay R3260 connects the supervisory lead C2568 to ground, thereby to energize the rear supervisory lamp 2603 in a circuit which includes the contacts 2539, the cam springs 2658, and the contacts 2644. The energization of this lamp serves to inform the operator handling the call that it has been routed to the desired destination under the control of the impulse sender 21A.

When the call is answered at the called substation or operator switchboard, the E. C. wiper 2408 is disconnected from ground in the last switch of the train, whereby the rear supervisory relay R3260 is deenergized and restores. In releasing, this relay disconnects the supervisory lead C2568 from ground, thereby to deenergize the rear supervisory lamp 2603. In releasing, the relay R3260 also opens its contacts 3262 to deenergize the winding of the relay R3300. When the lamp 2603 is deenergized, the operator handling the call is informed that the call has been answered at the called end thereof.

After setting up a connection over the rear end of the link 15 in the manner just explained, the operator at the first position of the switchboard 11 may hold this connection and extend a connection over the front end of the link to another called substation or operator switchboard by releasing the dial rear key 4100 and then operating the key set 22 to dial over the front end of the link 15. When the dial rear key 4100 is restored to normal, the contacts 4104 thereof are opened to deenergize the cut-in relay R3320. At the contacts 4103 of the key 4100, the marking lead C4133 is disconnected from ground. At the contacts 4102 of this key, the emergency start lead C4131 is disconnected from ground to deenergize the start relay R3210. At the contacts 4101, the previously traced operating circuit for the error relay R3220 is prepared. At the contacts 4105 the path shunting the winding of the relay R3300 is opened.

The start relay R3210, upon restoring, opens its contacts 3213 further to interrupt the previously traced alternative operating circuit for the sender start relay R3430. At its contacts 3212, the relay R3210 opens one of the operating circuits for the call lock relay R3040. At its contacts 3211, the relay R3210 opens another point in the path for impressing ground potential upon the lead C3214 extending to the link distributor 19.

The slow-to-release cut-in relay R3320, upon restoring, closes its contacts 3321 to reprepare the locking circuit for the dial rear relay R3340. At its contacts 3322, the relay R3320 opens another point in its own locking circuit. At its contacts 3323, the relay R3320 reprepares the operating circuit for the relay R3340. At its contacts 3325, the relay R3320 recompletes the initially traced operating circuit for the sender start relay R3430. Thus the sender control circuit 20, the impulse sender 21A, and the digit registers 21B are again seized in a manner which will be clearly apparent from the preceding explanation. Incident to the seizure of the control circuit 20, the previously traced operating circuit for the start send relay R2650 of the link 15 is completed, whereby the sender control circuit is operatively associated with the front end of the link 15. After the sender control circuit 20 has been reseized and the start send relay R2650 operated, the operator handling

10 the call may set up a connection over the front end of the link 15 in the exact manner explained above. When the two connections, as respectively set up through the front and rear ends of the link 15, are fully completed, the operator handling the call may retire from the connection by operating the disconnect key 4005 to cause the release of the position circuit 18, in the manner previously described.

If the operator so desires, she may, after completing a connection over the rear end of the link 15, disconnect the position circuit 18 from this link so that it may be used in handling another call, without releasing the connection as set up

15 over the rear end of the link 15, and before extending a connection over the front end of the link. To this end, the disconnect key 4005 is operated to cause the release of the relays R3040, R3050, R2630, R2560, R2530 and R3250 in

20 a manner which will be clearly apparent from the preceding description. After the enumerated relays are released only the relays R2480, R2440 and R2520 are operated in the link 15. In this regard it will be noted that with the relays R2440 and

25 R2520 operated and the relay R2530 released, the rear supervisory lamp 2603 is connected to be controlled over the E. C. wiper 2408, over a path which includes the contacts 2441, the normal post springs 2420, the contacts 2532, the cam springs

30 2658, and the contacts 2644. Accordingly, this lamp may be controlled from the called end of the connection to provide switchhook supervision or to transmit a disconnect signal to the operator handling the call at the first position of the

35 switchboard 11.

Incident to the release of the operator position circuit 18, and more specifically when the sender seize relay R3250 restores, the contacts 3255 are opened to deenergize the sender start relay R3430

40 of the sender control circuit 20. When this start relay releases the indicated control circuit, the impulse sender 21A, the digit registers 21B, and the start send relay R2650 of the link 15 are all released, in a manner which will be clearly ap-

45 parent from the preceding explanation. Thus the connection as set up over the rear end of the link 15 may be held on this link while the operator utilizes the position circuit 18 to attend to other calls. In this regard it will be under-

50 stood that by operating the talk key 2550 during an interval when the position circuit 18 is idle, the operator may re-enter the connection as set up over the rear end of the link 15 and dispose of the call in any desired manner. Alternatively,

55 the operator may, by operating the link release key 2556 to short-circuit the locking winding of the change-over relay R2480, effect the release of the link 15 and the succeeding switches in the train in an obvious manner.

60 From the preceding explanation it will be understood that when the dial rear key 4100 is operated during an interval when the position circuit 18 is idle, a distributor selected link associated with the first position of the switchboard is seized. It will also be understood that the seized link, such, for example, as the link 15, the position circuit 18, and the sender control circuit 20, are all prepared for the transmission of switch directing impulses over the rear end of the link when this key is operated. Accordingly, if the operator, in actuating the key 4100, seizes the link 15, for example, with the intention of setting up a call between two subscribers by first routing a connection to one subscriber over one end of the link and then routing another connection to a second subscriber

over the other end of the link, the first connection must necessarily be set up over the rear end of the link. After this connection is completed, the operator may release the dial rear key 4100 to cause the reseizure of the sender control circuit 20 and the impulse sending equipment, and then dial over the front end of the link for the purpose of setting up the second connection.

The other case in which the facilities for dialing over the rear end of a link must be used is that in which the operator may, for one reason or another, find it necessary to release a connection as extended to the switchboard 11 from a calling substation or operator switchboard over the rear end of the link 15 while holding a connection as extended to a called subscriber or operator switchboard over the front end of the link. This operating sequence may be effected by first operating the release rear key 4060 to release the rear end of the link 15, for example; restoring the release rear key to normal; and then actuating the dial rear key 4100 to its off-normal position. The relay operations resulting from the operation of the dial rear key 4100 in a case of this character are exactly the same as described above. If the link 15 is occupied with a call, the relays R2630, R2650 and R2620 are operated therein after the release rear key 4060 is operated and then released. Accordingly, when the dial rear key 4100 is energized to cause the operation of the relays R3210, R3340, R3350 and R3200, and the seizure of the sender control circuit 20 and the impulse sending equipment, all in the manner explained above, only the start relay R2530 of the link 15 is energized in direct response to operation of the dial rear key. This start relay, in operating, effects the operation of the answer switch 16 to seize an idle delayed call selector in the exact manner explained above. After this selector is seized, the desired connection may be extended to its destination and the sender control circuit and associated sending equipment released in the manner described above.

Error in dialing

If the operator in handling a call involving the position circuit 18, the link 15, the sender control circuit 20, and the register sender 21 discovers that she has committed an error in dialing, either through the front or the rear end of the link, she may actuate the error key, not shown, of the key set 22. In response to this operation, the error lead is connected to ground to complete a circuit through the contacts 3632' for energizing the error relay R3410 of the sender control circuit 20. This relay, in operating, locks to the grounded error lead through its contacts 3414 and also locks to ground through the contacts 3415 and 3401'. At its contacts 3413, the relay R3410 deenergizes the hold relay R3620. At its contacts 3412, the relay R3410 deenergizes the sender connect relay R3700. At its contacts 3411, the relay R3410 completes an obvious circuit for energizing the error relay R3220 of the position circuit 18. The sender connect relay R3700, upon restoring, opens its contacts 3701 to 3709, inclusive, thereby to disconnect the register sender 21 from the sender control circuit 20. In response to this operation, the impulse sender 21A and the digit registers 21B of the registering sender are released in an obvious manner. In releasing, the sender connect relay R3700 also deenergizes the sender supervisory relay R3640.

The error relay R3220 of the position circuit 18, in operating, opens its contacts 3222 and 3223

to interrupt the completed operating and locking circuits for the sender start relay R3430, causing the latter relay to restore. The sender start relay R3430, upon restoring, opens its contacts 3432 to deenergize the connect relay R3400. Assuming that the connection is being extended through the front end of the link, the relay R3400, upon restoring, opens its contacts 3405 to deenergize the start send relay R2650 of the link. At its contacts 3401', the relay R3400 opens one of the established locking circuits for the error relay R3410. At its contacts 3402', the relay R3400 reprepares the operating circuit for the sender start relay R3430. Shortly following the release of the connect relay R3400, the slow-to-release hold relay R3620 restores. Following the release of the latter relay the sender control circuit 20 is fully restored to normal.

The start send relay R2650, upon releasing, disconnects the control lead of the trunk extending to the call switch 17 from ground, whereby this switch and any succeeding operated switches are released in the usual manner. The remaining circuit switching operations which occur incident to the release of the start send relay R2650 are without effect.

When the error key of the key set 22 is released, the error lead is disconnected from ground to deenergize the error relay R3410 of the control circuit 20. This relay, in restoring, opens its contacts 3411 to deenergize the error relay R3220 of the position circuit 18. The latter relay, upon releasing, closes its contacts 3223 to recomplete the operating circuit for the sender start relay R3430. When the latter relay reoperates the sender control circuit 20 and the register sender 21 are reseized in the exact manner explained above. Incident to the reseizure of the sender control circuit 20, and more specifically when the connect relay R3400 reoperates, the operating circuit for the start send relay R2650 is recompleted at the contacts 3405. This relay, in reoperating, functions to reseize the call switch 17. Following the reseizure of this switch, the connection may be re-routed to the desired destination by again keying up the directory number designating the destination of the key set 22.

In the event the dialing error occurs incident to the extension of a connection over the rear end 50 of the link 15, i. e., through the answer switch 16, this end of the link and any operated switches which succeed the answer switch 16 are released in response to the operation of the error relay R3220. In this case the dial rear relays R3340 and R3350 are operated during the interval when the error relay R3220 is energized. Accordingly, a path including the contacts 3343 and 3221, C2579, and the contacts 2569 is completed for short-circuiting the locking winding of the change-over relay R2480 and the winding of the sender seize relay R3250 when the error relay R3220 operates. In operating, the error relay R3220 also opens its contacts 3222 to interrupt the established locking circuit and a point in the operating circuit for the sender start relay R3430, thereby to effect the release of the sender control circuit 20 in the manner pointed out above. The relay R3250, upon restoring, disconnects the start lead C2580 from ground to effect the release of the link start relay R2530 in the manner previously explained.

When the two relays R2530 and R2480 restore, the answer switch 16 and any operated switches which follow are released in the manner previously explained. Thereafter and when the error key of the key set 22 is restored to normal to

cause the sequential release of the error relay R3410 in the control circuit 20 and the error relay R3220 in the position circuit 18, operation of the answer switch 16 to seize an idle one of the delayed selectors to which it has access is again initiated. Thus when the error relay R3220 restores, it recloses its contacts 3222 to reconnect the link start lead C2580 to ground and thus cause the reoperation of the start relay R2530. When the conditions now under consideration prevail, the dial rear key 4100 is operated. Accordingly, the first contact of the level marking contact set 2410 is marked with ground potential so that the answer switch 16 is operated to select an idle delayed call selector during the hunting operation thereof. After this selector is seized, and more specifically when the switching relay R2440 of the answer switch 16 operates, the operating circuit for the sender seize relay R3250 is again completed. In releasing, the error relay R3220 also closes its contacts 3222 to recomplete the operating circuit for the sender start relay R3430. When this start relay reoperates, the sender control circuit 20 and the register sender 21 are again seized in the exact manner explained above. Following the reseizure of these two units and the seizure of an idle delayed call selector the operator handling the call may reroute the call to its desired destination by keying up the correct directory number on the key set 22.

All trunks busy to the answer switch 16

In the event the answer switch 16, during the rotary movement thereof, fails to find a calling trunk circuit or to find a trunk extending to an idle delayed call selector as the case may be, the wipers thereof are rotated through eleven steps at which time the cam springs 2658 are disengaged, the cam springs 2659 are moved into engagement, and the cam springs 2418 are closed. At the cam springs 2658, the previously described circuits for controlling the rear supervisory lamp 2603 are opened. At the cam springs 2659, a circuit is completed for energizing the rear supervisory lamp 2603 in accordance with the ground pulses applied to the 120 I. P. M. lead C2637 by the pulsing cam 2685. The flashing of this lamp at the indicated rate of 120 flashes per minute serves to inform the operator handling the call at the first position of the switchboard that the answer switch 16 has failed in its assigned function to find a calling trunk circuit or an idle delayed call selector. At the cam springs 2418, an obvious circuit is completed for energizing the switching relay R2460. This relay, in operating, locks to ground through its contacts 2465 and opens its contacts 2461 to interrupt the operating circuit for the rotary magnet 2412. Thus the rotary movement of the wipers 2401 to 2408, inclusive, is arrested. In operating, the relay R2460 also closes its contacts 2462 to energize the sender seize relay R3250, whereby the sender control circuit 20 and the associated register sender are seized in the manner previously explained.

The operator, upon observing the flashing of the lamp 2603, may release the position circuit 18, the sender control circuit 20, and the link 15 by first operating the disconnect key 4005 and then operating the link release key 2556. When the disconnect key 4005 is moved off normal, the position circuit 18 is disconnected from the link 15, the sender control circuit 20 and the register sender 21 are released in a manner which will be clearly apparent from the above explanation. When the position circuit 18 is disconnected from

the link 15, the relays R2630, R2560, R2530 and R2520 are deenergized in the link. Thereafter and when the link release key 2556 is operated to its off-normal position, the locking winding of the change-over relay R2480 is deenergized, causing this relay to restore. In releasing, the relay R2480 effects the release of the answer switch 16 in the exact manner explained above. Incident to the release of the switching mechanism incorporated in this switch, the cam springs 2418 are opened to deenergize the switching relay R2460, the cam springs 2659 are opened to prevent further ground pulses from being transmitted to the rear supervisory lamp 2603, and the cam springs 2658 are closed to reprepare the previously traced supervisory circuits over which this lamp may be controlled.

All trunks busy to the call switch 17

20 In the event the call switch 17, during its rotary movement, fails to find an idle trunk in the selected group of trunks, the wipers thereof are rotated through eleven steps wherein cam springs are closed to arrest the rotary movement of the call switch wipers and to complete a path for connecting the 120 I. P. M. lead C2637 to the E. C. lead of the trunk extending to the call switch. Assuming that the illustrated Y wiring is not provided in association with the common pulsing lead C2637 and the pulsing element 2685, only ground pulses are transmitted over the E. C. control path. These ground pulses as transmitted over the lead C2663 to the sender control circuit 20 are without effect to arrest or otherwise interfere with the operation of the register sender 21 to transmit the remaining digits of the directory number as registered in this sender through operation of the key set 22. It is noted, however, that the impulses of the digits transmitted from the register sender 21 are absorbed in the call switch 17 without effecting further operation of this switch or any of the switches to which it has access. After the impulse transmission is completed, and incident to the release 45 of the sender control circuit and the register sender 21 in the manner previously explained, the operating circuit for the cut-through relay R2620 of the link is completed. In operating, the cut-through relay closes its own locking circuit and, 50 at its contacts 2624, closes a circuit over which the ground pulses applied to the E. C. lead of the trunk extending to the call switch 17 are utilized to effect the intermittent operation of the front supervisory relay R2600. This relay 55 functions to repeat the ground pulses to the front supervisory lamp 2516 through its contacts 2601. Also incident to the operation of the cut-through relay R2620, the relay R3230 is operated to open the operating and locking circuits for the sender 60 start relay R3430 and thus permit the sender control circuit 20 to be fully released. Incident to the release of this circuit, the start send relay R2650 of the link 15 is deenergized and restores.

65 The operator handling the call, upon observing the flashing lamp 2516, is informed that an all-trunks-busy condition has been encountered either in the call switch 17 or one of the succeeding switches of the train. Upon receiving 70 this signal, the operator may, by actuating the release front key 4070, effect the release of the call switch 17, the cut-through relay R2620, and the relay R3230. Thus when this key is moved off normal, the split call relay R3150 is operated 75 in the position circuit 18; a circuit including

the lead C4084 is completed for sustaining the energization of the relay R3230; and a path including the two leads C4084 and C2577 and the contacts 2567 is completed for short-circuiting the winding of the cut-through relay R2620. In releasing, the relay R2620 opens its contacts 2624 to discontinue the intermittent operation of the front supervisory relay R2600 and the consequent flashing of the front supervisory lamp 2516. At its contacts 2628, the relay R2620 opens its own locking circuit and the previously traced circuit for energizing the relay R3230. At its contacts 2629, the relay R2620 disconnects the control conductor of the trunk extending to the call switch 17 from ground, whereby this switch is released in the usual manner.

When the release front key 4070 is restored to normal, the split call relay R3150 is released and the lead C4084 is disconnected from ground to deenergize the relay R3230. The last-mentioned relay, upon restoring, closes its contacts 3231 to recomplete the operating circuit for the sender start relay R3430, whereby the sender control circuit 20 and the impulse sender 21A are re-seized and the start send relay R2650 of the link 15 is reoperated. From this point on, the operator handling the call may re-extend the connection to the desired point, in the manner previously explained.

All links busy at an operator position

As previously indicated, when all of the links associated with the first position of the switchboard 11 become busy, the lead C3045 is disconnected from ground to deenergize the all-links-busy relay R3020 in the position circuit 18. In releasing, this relay opens its contacts 3022 to deenergize the operated relays of the link distributor 19. At its contacts 3021, the relay R3020 also opens a point in the previously traced operating circuit for the start relay R3310. In this regard it is noted that the lead C3045 is disconnected from ground in the last link taken for use. More specifically, when the position start relay R3210 operates to seize this link, the relay R3040 is energized and locked up. With the relay R3040 in its operated position a circuit through the contacts 3044 is completed for sustaining the energization of the start relay R3310. Accordingly, this relay and the position start relay R3210 are prevented from releasing to cause the premature release of the seized link. Thereafter and when the position circuit 18 is disconnected from the last link, such, for example, as the link 15, the relay R3040 is deenergized in the manner previously explained. This relay, in releasing, opens its contacts 3044 to interrupt the multiple circuit for energizing the start relay R3310. With the two relays R3020 and R3040 restored, the start relay R3310 cannot be reoperated to effect the seizure of another line. Moreover, with the relay R3310 released, the position circuit 18 is marked as busy in the position distributor 13 and the start lead C3963 is disconnected from ground in this circuit.

When the all-busy condition of the links associated with the position circuit 18 is terminated, the all-links-busy relay R3020 is again energized to reprepare the operating circuit for the start relay R3310 and to cause the link distributor 19 to select an idle link in the manner explained above.

DELAYED CALLS

After a call is answered at one of the positions of the switchboard 11, the operator attending the

answering position normally extends the call to the desired destination in the manner previously explained. If, however, the called party cannot be located, the calling party is advised that the call may not immediately be completed and that when the connection has been extended to the desired destination he will be recalled. The answering operator then prepares a ticket for the call, indicating the calling and called substations, which ticket is used for reference purposes is subsequently setting up the desired connection on a point to point basis. Usually, point to point calls of this type are handled at a specific one of the operator positions. Accordingly, the operator who answers such an unsuccessful call, after ticketing the call, passes the ticket to the operator attending the position which is assigned to handle the point to point calls. The point to point operator then endeavors to establish a connection from her position to the called subscriber substation and, after this connection is established, to establish a second connection from her position to the calling subscriber substation. This type of call is variously termed a delayed, point to point, or tail to tail call, and will hereinafter be referred to as a delayed call.

Assuming that the operator attending the illustrated first position of the switchboard is assigned to handle delayed call traffic and that she desires to reach the called substation C, for example, on a call originating in the area served by the manual office No. 1, she first operates the delayed call key 4025 to its off-normal position, thereby to interrupt the previously traced operating circuit for the start relay R3310. This relay, in releasing, opens the distributor controlled operating circuit for the position start relay R3210; disconnects the start lead C3963 from ground in the position circuit 18, and connects the position guard lead C3962 to ground through its contacts 3313. Thus the position circuit 18 is marked against distribution in the position distributor 13 and no calls can be routed thereto under the control of the common start circuit 12.

After thus marking the position circuit 18 against the receipt of incoming C. L. R. and inward toll calls, the operator may actuate the dial rear key 4100 for the purpose of seizing the link allotted to the use of the position circuit 18, by the link distributor 19 and for the additional purpose of causing the answer switch of this link to seize an idle one of the delayed call selectors, all in the manner previously explained. In this regard it may be assumed that the link 15 and the delayed call selector 47 are seized from the position circuit 18 in response to the operation of the dial rear key 4100. Incident to the operation of this key, the position circuit 18 is prevented from receiving inter-position calls in the manner previously described. Also incident to the operation of this key, the sender control circuit 20 and the register sender 21 are seized and conditioned for the transmission of impulses over the rear end of the link 15. When the sender pilot lamp 4125 is energized to indicate that the sender control circuit 20 and the register sender 21 have been seized, the operator handling the call may key up the digits of the directory number designating the desired substation C and then actuate the disconnect key of the key set 22. In response to these operations the register sender 21 functions to transmit the keyed digits over the rear end of the link 15 for the purpose of directing the call to the desired substation C. In this regard it will be understood that the first digit

transmitted by this sender is utilized in the seized delayed call selector, such, for example, as the selector 41, to direct this selector in its operation to seize one of the front conversion selectors of the switch train, such, for example, as the selector 55. The second digit is utilized to direct the selector 55 in its operation to select an idle first switch in the train 58. The remaining digits of the directory number are first transmitted through the register selector 56 to an idle register sender, such, for example, as the register sender 57, which receives the incoming impulses as loop impulses and functions to retransmit these impulses to the switches of the train 58, for example, under the revertive control of the switching mechanisms respectively provided in the switches of this train. After all of the registered digits have been transmitted by the register sender 21, this sender and the sender control circuit 20 are released in the manner previously explained. Incident to the release of the control circuit 20, the cut-in relay R3320 of the position circuit 18 is operated to effect the release of the dial rear relays R3340 and R3350, the split answer relay R3200 and the dial rear lock relay R3240. Also incident to the release of the sender control circuit 20, the sender pilot lamp 4125 is deenergized to inform the operator that the impulse transmitting operation has been completed.

When the call has been extended through the answer switch 16 the delayed call selector 41, the selector 55 and the succeeding switches of the train 58 to the line serving the substation C, the last switch of the train operates to its ringing setting wherein a path is completed for connecting the E. C. wiper 2408 of the answer switch 16 to ground. When this wiper is connected to ground and the dial rear relay R3340 is released in the position circuit 18, the rear supervisory relay R3260 is energized over the previously traced circuit to complete a circuit through its contacts 3261 for energizing the rear supervisory lamp 2603. When the call is answered at the called substation C, the last switch in the train 58 is shifted to its call answered setting. Incident to this operation, the E. C. wiper 2408 is disconnected from ground to effect the deenergization of the rear supervisory relay R3260 and the rear supervisory lamp 2603. Also incident to this operation, a talking circuit is completed between the called substation C and the operator headset 2901, 2902, whereby the operator may converse with the called subscriber and ask this subscriber to hold the connection until the calling party is reached.

After locating the called party at the substation C, the operator may release the dial rear key 4100, thereby to effect the release of the cut-in relay R3320. Incident to the release of this relay, the sender control circuit 20 and the register sender 21 are reseized in the manner previously explained. In this case, the relays R3240, R3320, R3340 and R3350 are deenergized in the position circuit 18. Incident to the reseizure of the sender control circuit 20, the start send relay R2650 of the link 15 is energized. Accordingly, the register sender 21 is operatively associated with the front end of the link 15. Also incident to the reseizure of the control circuit 20, the sender pilot lamp 4125 is again energized. Upon observing that this lamp is illuminated, the operator may actuate the digit keys of the key set 22 in accordance with the directory number designation of the operator handling the call in the manual office No. 1. The keyed digits as transmitted

by the register sender 21 are utilized to set up a toll switch train over which the call is forwarded to the operator switchboard 41 in the manual office No. 1. In the case under consideration, 5 this train will comprise only the call switch 17 and the trunk circuit 28, terminating one of the ring-down trunks extending to the operator switchboard 41. Accordingly, only one digit is registered in the register sender 21 and this digit is utilized to direct the call switch 17 in its operation to seize a trunk circuit terminating an idle one of the trunks extending to the switchboard 41. If the trunk circuit 28 is utilized in the connection, this trunk circuit, when seized, functions to connect the E. C. conductor of the trunk extending to the call switch 17 to ground. In this regard it will be recalled that the sender control circuit 20, the register sender 21, and the start 10 send relay R2650 of the link 15 are released after the single digit designating the group of trunks extending to the manual office No. 1 is transmitted by the register sender. It will also be recalled that incident to the release of the sender control circuit 20, the cut-through relay R2620 15 is energized and locked in its operated position. Accordingly, when the E. C. conductor of the trunk extending to the call switch 17 is connected to ground, the front supervisory relay R2600 is energized and operates to complete the above-described circuit for energizing the front supervisory lamp 2516. Energization of this lamp serves to inform the operator handling the call at the first position of the switchboard 11 that 20 an idle trunk has been seized. This operator may now actuate the ring front key 4050 for the purpose of transmitting ringing current to the ring-down trunk circuit 28, whereby an incoming call signal is produced at the operator switchboard 41 in the manual office No. 1. When the operator at this switchboard answers the call, she may extend the call to the desired substation in the manner conventionally followed in manual office practice. After the desired connection to 25 the called substation served by the manual office No. 1 is established the operator handling the call at the switchboard 11 may retire from the connection by operating the disconnect key 4005 to effect the release of the position circuit 18, in 30 the manner previously described.

The operator at the first position of the switchboard 11 in handling certain types of delayed calls may desire not to ring the called subscriber until the calling subscriber has been relocated. 35 For example, if this operator is handling a relatively stale delayed call involving the substation C as the calling substation and a tributary C. A. X subscriber substation as a called substation, it may be desirable not to signal the 40 called subscriber until the calling subscriber is relocated. In this case, the called tributary C. A. X line is selected and seized through the rear end of the link 15, for example, but the operator in keying up the directory number of 45 the called substation omits the last digit. This digit is, in accordance with conventional practice, utilized to set the frequency or code selecting switch of the C. A. X connector occupied with the call. Also in accordance with conventional practice, this connector will not shift to its ringing setting until the frequency or code selecting digit is received thereby. After all but the last digit of the indicated directory number are registered in the register sender 21, the disconnect 50 key of the key set 22 is operated, and the regis-

ter sender completes its operation to transmit the registered digits, this sender, the control circuit 20, and the four relays R3200, R3240, R3340 and R3350 are all released. Incident to the release of the sender control circuit 20, the cut-in relay R3320 is operated in the position circuit 18. The dial rear relay R3340, upon restoring in response to the release of the sender control circuit 20, closes the circuit through its contacts 3342' for energizing the rear supervisory relay R3260, whereby the rear supervisory lamp 2603 is energized in the link 15. In this regard it is noted that when the called line is reached through the switch train of the distant C. A. X, a signal is transmitted to the answer switch 16 from the C. A. X switch train which indicates that the called line has been selected. More specifically, when this line is selected the E. C. wiper 2408 of the answer switch 16 is connected to ground in a succeeding switch of the train to effect the operation of the rear supervisory relay R3260. The energization of the front supervisory lamp 2516 informs the operator handling the call at the switchboard 11 that the called line has been reached. After receiving this information, she may restore the dial rear key 4100 to normal, thereby to effect the reseizure of the sender control circuit 20 and the register sender 21, and the association of these two units with the front end of the link, i. e., the call switch 17, in the manner previously explained. When the key 4100 is restored to normal, the contacts 4105 thereof are opened to interrupt the path shunting the winding of the relay R3300. When thus fully energized the relay R3300 operates and closes its contacts 3301 to prepare a path for impressing negative battery potential upon the rear talking lead C2575. At its contacts 3302, the relay R3300 opens a point in the path including the resistor 4106 for shunting current from its own winding. After a connection is established through the front end of the link to the called substation C through directive re-operation of the register sender 21, and this sender and the sender control circuit 20 are released, the operator handling the call may reactivate the dial rear key 4100 in order to reassociate the control circuit 20 and the register sender 21 with the connection extending through the rear end of the link 15 to the called C. A. X subscriber line. When the key 4100 is reoperated to its off-normal position, a path including the resistor 4106, the contacts 4105, C4135, and the contacts 3301 and 3202 is completed for impressing negative battery potential upon the rear talking lead C2575. Also incident to the operation of this key, the dial rear relay R3340 is operated to deenergize the rear supervisory relay R3260. In releasing, this supervisory relay opens its contacts 3262 to deenergize the relay R3300. Accordingly, the relay R3300 restores shortly after the key 4100 is returned to its off-normal position. The negative battery pulse thus transmitted over the rear talking lead C2575 and the lower talking wiper 2402 of the answer switch 16 is utilized to condition the C. A. X trunk repeater included in the reconnection to receive dial impulses. In this regard it will be understood that when the sender pilot lamp 4125 is again energized to indicate that the register sender 21 and the sender control circuit 20 have been reseized, the operator handling the call may key up the ringing digit of the directory number designating the called substation and then operate the disconnect key of the key set 22 for the purpose of releasing the

register sender and the sender control circuit after the ringing digit is transmitted by the sender. As previously indicated, this digit is utilized in the last switch of the C. A. X switch train to position the frequency or code selecting switch in accordance with the code or frequency which is utilized in signaling the desired substation.

After the register sender 21 has cleared itself of the ringing digit registered therein, this unit, the sender control circuit 20, and the four relays R3200, R3240, R3340 and R3350 are released. Incident to the release of the relay R3340 the rear supervisory relay R3260 is reoperated to again energize the rear supervisory lamp 2603. Also incident to the release of the sender control circuit 20 the cut-in relay R3320 is operated to perform the functions described above.

When the call is answered at the called C. A. X substation, the E. C. wiper 2408 of the answer switch 16 is disconnected from ground to effect the deenergization of the rear supervisory relay R3260 and the lamp 2603, whereby the operator handling the call is informed that it has been answered. The operator may now release the dial rear key 4100 to effect the release of the cut-in relay R3320 and actuate the disconnect key 4005 for the purpose of releasing the operator position circuit 18.

30 INTERPOSITION TRUNK CALLS

As previously indicated, the first two positions of the switchboard 11 are the only two positions of the board which may receive inter-position trunk calls. These two switchboard positions may receive such calls through the trunk circuit 24 and the corresponding inter-position trunk circuits from the remaining six positions of the switchboard, from the toll switchboard 30 or directly from the inter-toll dial train on a call originating in a distant office. In general, the manner in which such calls are handled at the first two positions of the switchboard will be clearly apparent from the preceding explanation in which the operation of the position circuit 18, the link 15, the sender control circuit 20 and the register sender 21 are considered in detail. It is noted, however, that inter-position calls have preference over C. L. R. and inward toll calls insofar as the call answering facilities provided at the first two positions of the switchboard 11 are concerned. In considering this type of call, it may be assumed that the position circuit 18 has been allotted to receive an incoming call by the position distributor 13, that the relay R3950 is operated in the position distributor 14 so that this position is also allotted to receive an inter-position trunk call, and that such an inter-position call is routed to the switchboard 11 through the trunk circuit 24 before the position circuit 18 and one of its associated links are seized by the common start circuit 12. It may be assumed further that the illustrated link 15 has been selected for use by the link distributor 19, so that the operating circuit for the connect relay R2630 is prepared through the contacts 3811 of the distributor relay R3810.

When the call is extended to the trunk circuit 24, the seizure relay of this trunk circuit operates to energize its associated marking relay in series with the position start relay R3210 of the position circuit 18. The circuit over which these two relays are energized in series may partially be traced as extending from ground through 70 make contacts controlled by the seizure relay of

the trunk circuit 24, the operating winding of the marking relay in this trunk circuit, the emergency start lead C3969 individual to this trunk circuit, the contacts 3958, C4131, the contacts 3032, and the winding of R3210 to battery. When energized in this circuit, the marking relay of the trunk circuit 24 operates, locks up and connects the two marking leads C3967 and C3968 to ground. The level marking lead C3967 is connected through the contacts 3954 of the operated distributor relay R3950 to the marking lead C4133, so that the first contact in the level marking contact set 2410 of the answer switch 18 is marked with ground potential to control the vertical movement of the answer switch 18. In this regard it will be understood that when the position start relay R3210 of the position circuit 18 operates, it closes the operating circuit for the link start relay R2530 to initiate the operation of the answer switch 18 in the manner previously explained. In operating, the link start relay R2530 also closes a prepared path for impressing ground potential upon the test wiper 2405 of the answer switch 18, this path extending from the grounded call marking lead C3968, by way of the contacts 3955, C3985, the resistor 2518, and the contacts 2537 to the wiper 2405. When this path is completed, the winding of the test relay R2430 is arranged to be short-circuited through the contacts 2484 when the change-over relay R2480 operates at the end of the vertical movement of the answer switch wipers. The purpose of providing this marking or short-circuiting path is to prevent the answer switch 18 from seizing an idle one of the delayed call selectors to which it has access during the rotary movement of its wipers. In other words, with this path completed the answer switch 18 can, during the rotary movement of its wipers, only search for the inter-position trunk circuit 24 which is occupied with a call, the answer switch 18 being effectively blocked against gaining access to the delayed call selectors. From this point on the manner in which the call is extended to the position circuit 18 and is handled at the first position of the switchboard is exactly the same as explained above with reference to incoming C. L. R. and inward toll calls.

To consider the manner in which the first two positions of the switchboard 11 are allotted to receive interposition calls, it is pointed out that when these two positions are vacated or not in use, such that the battery feed relays of the associated position circuits are deenergized, both of the distributor relays R3940 and R3950 are deenergized. If now the jack 2903 is inserted in the plug 2904 to effect the energization of the relays R2910, R3020 and R3310 in the manner previously explained, a circuit is completed for energizing the distributor relay R3950. This circuit extends from ground by way of the contacts 2911, 3031, 3033, 3104, 3223, 3231, 3256 and 2931, C3964, the winding of R3950, the contacts 3953, 3941 and 3951, and the resistor 3957 to battery. When thus energized, the relay R3950 first locks to battery through its contacts 3952 and the resistor 3957 and then opens its contacts 3951 and 3953 to interrupt two points in its own operating circuit. At its contacts 3951, the relay R3950 also opens a point in the operating circuit for the other distributor relay R3940. At its contacts 3955 and 3956, the relay R3950 connects the leads C3968 and C3969, which are common to the inter-position trunk circuits, to the leads C3965 and C4131 of the operator position circuit 18. At its contacts 3954, the relay R3950 prepares the

above-traced path for impressing ground potential upon the first contact of the level marking contact set 2410 as provided in each of the answer switches of the links associated with the first and second positions of the switchboard 11. Thus it will be apparent that with the distributor relay R3950 operated, the operator position circuit 18 is assigned to handle the first inter-position trunk call received at the switchboard 11. If a call of any type is extended to the position circuit 18 at a time when the second position of the switchboard is attended and idle, the distributor relay R3950 is released and the associated relay R3940 is operated to allot the second position of the switchboard to receive the next incoming inter-position call. In this regard it will be noted that the operating and locking circuits for the relay R3950 includes the break contacts 3256, 3231, 3223 and 3033, which are respectively controlled by the relays R3250, R3230, R3220 and R3030. Accordingly, when any one of these relays is operated in the manner previously explained, the distributor relay R3950 is deenergized and restores. In releasing, this relay closes its contacts 3951 to prepare or complete the operating circuit for the distributor relay R3940. At its contacts 3952, the relay R3950 opens a point in its own locking circuit. At its contacts 3951 and 3953, the relay R3950 reprepares its own operating circuit. At its contacts 3954, the relay R3950 opens the prepared path for impressing ground potential upon the marking lead C4133 extending to the first contact of the level marking contact set as provided in each of the answer switches 35 associated with the first two positions of the switchboard. At its contacts 3955 and 3956, the relay R3950 disconnects the leads C3968 and C3969 from the position circuit leads C3965 and C4131. 40 If the second position of the switchboard 11 is idle at the time the distributor relay R3950 restores, the guard lead C3964' individual thereto is connected to ground so that the relay R3940 is operated in a circuit which includes the contacts 3943, 3941 and 3951, and the resistor 3957. On the other hand, if the second position of the switchboard 11 is busy at the time the distributor relay R3950 restores, the guard lead C3964' is disconnected from ground to prevent the energization of the distributor relay R3940. With the two relays R3940 and R3950 released, the leads C3968 and C3969 common to the inter-position trunk circuits and utilized in the routing of calls to the first two positions of the switchboard, 55 are disconnected from the position circuits respectively provided at the first two positions of the board, and the marking lead C4133 is disconnected from the level marking lead C3967. If energized in response to the release of the first distributor relay R3950, the second distributor relay R3940 locks to battery through its preliminary make contacts 3942, the contacts 3951 and the resistor 3957. At its contacts 3941 and 3943, the relay R3940 opens two points in its own operating circuit. At its contacts 3941, the relay R3940 also opens a point in the operating circuit for the relay R3950. At its contacts 3944, the relay R3940 connects the level marking lead C3967 to the marking lead C4133 to prepare the above-described path for impressing ground potential upon the first contact of each level marking contact set as provided in the answer switches associated with the first two positions of the switchboard. At its contacts 3945 and 3946, the relay R3940 connects the two leads

C3968 and C3969 to the operator position circuit provided at the No. 2 position of the switchboard 11. When the No. 2 position of the switchboard 11 subsequently receives a call, the guard lead C3964' is disconnected from ground in the position circuit associated with this operator position to deenergize the distributor relay R3940. In releasing, this relay opens its own locking circuit, prepares or completes the operating circuit for the first distributor relay R3950, disconnects the two marking leads C3967 and C4133 from each other, and opens its contacts 3945 and 3946 to disconnect the leads C3968 and C3969 from the position circuit provided at the second position of the switchboard. It will be observed that, so long as the relay R3940 remains operated, the first distributor relay R3950 cannot be energized even though the position circuit 18 becomes idle before an inter-position trunk call is received at the switchboard. Thus in the normal operation of the system the inter-position trunk calls will be rotated between the first two positions of the switchboard 11.

Supervision transfer

When an operator at one position of the switchboard 11 receives a call which must be transferred over one of the inter-position trunk circuits to another position of the switchboard equipped to receive inter-position trunk calls, supervision is transferred from the link associated with the answering operator position to the link which receives the call through the inter-position trunk circuit. In considering the manner in which the supervisory signals are repeated from one position of the switchboard to another, it may be assumed that a call which as been answered at the first position of the switchboard through the link 15 is transferred through the call switch 17 of this link and the inter-position trunk circuit 24 to the No. 2 position of the switchboard. Incident to the operation of the call switch 17 to select the group of trunks extending to the inter-position trunk circuits, and more particularly when the wipers of this switch are operated to the contact level corresponding to the inter-position trunk circuits, normal post springs are closed in this switch to complete a circuit through the contacts 2643 for energizing the upper winding of the supervisory relay R2640. When thus energized, the relay R2640 partially operates to open only its X contacts 2644, thereby to include its lower winding in the circuit for energizing the rear supervisory lamp 2603. At this time the start relay R2530 of the link 15 is operated, so that the circuit for controlling the rear supervisory lamp 2603 includes the signal lead C2568 and is held open at the contacts 3261 in the position circuit 18. After the connection has been fully transferred to the second position of the switchboard and the answering operator at the first position of the switchboard releases the position circuit 18, the start relay R2530 is deenergized so that the circuit for controlling the rear supervisory lamp 2603 is extended to include the contacts 2532', 2521 and 2484. This circuit is held open at the contacts 2521 so long as the calling party remains on the connection. With this circuit established, the supervisory relay R2640 may be controlled over the calling end of the connection to repeat disconnect supervisory signals through the trunk circuit 24 to the link occupied with the call at the No. 2 position of the switchboard. Thus if the calling subscriber or operator performs a connection release oper-

ation, the supervisory relay of the trunk circuit preceding the answer switch 16 operates to connect the test wiper 2405 to ground, thereby to short-circuit the lower winding of the supervisory relay R2520. This relay, in releasing, closes its contacts 2521 to energize the lower winding of the supervisory relay R2640. When its lower winding is thus energized the relay R2640 completes its operation. At its contacts 2641, the relay R2640 connects the E. C. conductor of the trunk extending to the call switch 17 to ground over a path which includes the contacts 2624 and 2534 and the resistor 2639. When this path is completed, a supervisory relay in the trunk circuit 24 operates to shunt down the lower winding of the supervisory relay in the link occupied with the call at the No. 2 switchboard position which corresponds to the relay R2520 of the illustrated link 15. When this supervisory relay of the second position link circuit releases, it shorts out its lower winding to prevent its reoperation, and closes a circuit for energizing its associated rear supervisory lamp, all in a manner which will be fully apparent from a consideration of the corresponding circuits in the link 15. Thus a disconnect signal is brought in to the operator handling the call at the No. 2 position of the switchboard. It will be noted that the front supervisory lamp 2516 is energized in parallel with the supervisory relay of the trunk circuit 24. The current flow through this lamp is, however, insufficient to cause the illumination thereof.

In operating, the relay R2640 also opens its contacts 2642 to interrupt the path for short-circuiting the lower winding of the supervisory relay R2520. Normally this circuit is held open at the normal post springs 2605 so that the opening of the contacts 2642 is without effect. At its contacts 2643, the relay R2640 opens the above-described circuit for energizing its own upper winding. If the connection release operation performed at the calling substation or operator position is followed by the recompletion of the calling circuit, the supervisory relay of the trunk circuit preceding the answer switch 16 operates to reconnect the test wiper 2405 to a low resistance battery path, whereby the supervisory relay R2520 is reoperated to deenergize the supervisory relay R2640 and the rear supervisory lamp 2603. In releasing, the relay R2640 opens its contacts 2641 to effect the release of the operated supervisory relay in the trunk circuit 24. At its contacts 2642, the relay R2640 reprepares the path for short-circuiting the lower winding of the supervisory relay R2520. At its contacts 2643, the relay R2640 re-completes the circuit for energizing its upper winding, whereby this relay is prevented from closing its X contacts 2644.

Succeeding supervisory signals transmitted to the supervisory relay R2640 from the trunk circuit preceding the answer switch 16 are not effective to control the rear supervisory lamp of the link occupied with the call at the No. 2 position of the switchboard since the disconnect supervisory signal is short-circuited within this link. The supervisory relays R2520 and R2640 together with the rear supervisory lamp 2603 of the link occupied with the call at the first position are, however, operative to follow the supervisory signals transmitted to the link over the test wiper 2405 from the preceding trunk circuit. In this regard it is again pointed out that the path short-circuiting the lower winding of the supervisory relay R2520 is, in the normal case, held open at the normal post springs 2605. If,

however, the call under consideration was initially extended to the switchboard 11 over a ring-down trunk extending to a distant tributary office, which trunk is directly accessible to the answer switch 16, the normal post springs 2605 are closed. In this case, the opening of the contacts 2642 by the relay R2640 prevents the lower winding of the supervisory relay R2520 from being short-circuited and thus permits the last-mentioned relay to follow the supervisory signals as repeated by the ring-down trunk circuit occupied with the call over the test wiper 2405 of the answer switch 16. From the foregoing explanation, it will be understood that if the calling party or operator attempts to recall an operator at the switchboard 11, a locked-in disconnect supervisory signal is produced at the No. 2 position of the switchboard and the flashing recall signal is only brought in at the first position of the switchboard through the intermittent energization of the rear supervisory lamp 2603.

Upon receiving the disconnect signal, the operator at the No. 2 position may release the link occupied with the call. Incident to this operation the supervisory relays of the trunk circuit 24 function to connect the E. C. wiper of the call switch 17 to ground over a low resistance path, whereby a circuit including the contacts 2624 and 2534 is completed for directly energizing the front supervisory lamp 2516. If the operator at the No. 1 position receives a steady disconnect signal on the front supervisory lamp 2516, unaccompanied by the flashing of the lamp 2603, she may release the connection in the exact manner previously explained. In this regard it will be understood that the supervisory relay R2640 is deenergized and restores in response to the release of the call switch 17. If, on the other, the steady disconnect signal produced by energization of the front supervisory lamp 2516 is accompanied by intermittent energization of the rear supervisory lamp 2603, the operator handling the call at the first position of the switchboard will normally operate the talk key 2550 to reenter the connection for the purpose of ascertaining the additional service desired by the calling subscriber or operator. In this case, the entire connection may be released under the control of the operator at the first position of the switchboard or the connection through the front end of the link may be released and a new connection established therethrough, all in accordance with the dictates of the calling subscriber or operator.

CALL FROM TOLL OFFICE NO. 1 TO THE CENTRAL OFFICE 10

In considering the manner in which toll calls originating in the distant toll offices are handled by the switching equipment provided in the central office 10, it may be assumed that a call is routed to the central office 10 over the trunk 5 from the toll switchboard in the toll office No. 1 to cause the seizure of the trunk circuit 26 at a time when the finder-selector link 35, as shown in Figs. 14, 15 and 16 of the drawings, is allotted for use by the link distributor 39. In this regard it is pointed out that when the trunk 5 is seized through the inter-toll switch train of the toll office No. 1 from the toll switchboard in this office, negative battery potential is impressed upon the two conductors of the trunk. The signal relay R320 of the trunk circuit 26 is energized and operates when the two conductors of the trunk 5 are connected to the negative terminal of the exchange battery provided in the

toll office No. 1. More specifically, the two lower windings of this relay are energized over a circuit which extends from ground by way of the contacts 544, 613, 583 and 575, the signal lead C325, 5 the winding of the retard coil 330, the middle winding of the relay R320, and the two repeating coil windings 305 and 306 in parallel to the two sides of the trunk 5 as connected to the negative terminal of the exchange battery in the 10 toll office No. 1. The two lower windings of the relay R320 are further energized over a circuit which extends from ground through the resistor 322, the two series-connected lower windings of R320, and the two repeating coil windings 305 15 and 306 to the two sides of the trunk 5. It will be observed that the upper winding of the signal relay R320 is normally energized over a circuit including the resistor 323. Accordingly, this relay is exceedingly sensitive to changes in the 20 energization of its two lower windings. When these two windings are energized over the circuits just traced, the signal relay R320 operates. If with the relay in its operated position the junction point between the two lower windings 25 thereof is connected to the negative terminal of the exchange battery provided in the central office 10, the relay remains in its operated position. On the other hand, if the two sides of the trunk 5 are connected to ground in the toll office No. 1, 30 the relay R320 is released, irrespective of whether ground or negative battery potential is impressed upon the junction point between its two lower windings.

In the toll office No. 1, the trunk 5 is terminated in a trunk circuit which may be substantially identical in arrangement with the illustrated trunk circuits 26 and 27. It will be understood, therefore, that a signal relay corresponding to the relay R320 and also connected 40 to be controlled over the simplex of the trunk 5, is utilized as the termination for the control circuits which commonly include the two lower windings of the illustrated signal relay R320 and the two sides of the trunk 5.

45 When the signal relay R320 operates in response to seizure of the trunk 5 in the toll office No. 1, it closes its contacts 321 to complete a circuit through the contacts 638 and 671 for energizing the pulse relay R660. The relay R660, 50 upon operating, bridges the lower winding of the loop seizure relay R650 across the talking conductors C775 and C776 of the trunk 26d extending to the banks of the finder 36, over a path which extends from the upper talking conductor C775 55 by way of the contacts 632, the repeating coil winding 313, the contacts 434 and 633, the lower winding of R650, the contacts 661, 631' and 432, the repeating coil winding 314, and the contacts 634 to the lower talking conductor C776. At its contacts 663, the relay R660 opens a point in the operating circuit for the slow-acting digit relay R730. At its contacts 662, the relay R660 prepares a path for unbalancing the loop as set up 60 between the trunk circuit 26 and a succeeding selector, and completes an obvious circuit for energizing the slow-acting hold relay R710.

The relay R710, upon operating, closes its contacts 712 to prepare the operating circuit for the digit relay R730. At its contacts 711, the relay R710 completes an obvious circuit for energizing the hold slave relay R720. The relay R720, upon operating, closes its contacts 722 to connect the winding of the cut-off relay R750 to the test lead C777 of the trunk 26d, whereby the rotary position of this trunk is marked in the banks of the

finders to which it is accessible, and a circuit is prepared for energizing the cut-off relay R150 when the assigned finder 36 operates to seize the trunk 26d. At its contacts 723, the relay R120 connects the test lead C179 of the trunk 26f to ground, thereby to mark this trunk as busy in the banks of the toll selectors to which it is accessible. At its contacts 724, the relay R120 opens a point in the operating circuit for the seizure relay R640. At its contacts 725, the relay R120 prepares locking circuits for the two switching relays R430 and R440. At its contacts 726, the relay R120 completes a circuit for energizing the lower winding of the supervisory relay R540, this circuit extending from ground by way of the contacts 726, 423 and 745, and the lower winding of R540 to battery. At its contacts 727, the relay R120 opens a point in the operating circuit for the seizure relay R760, thereby to guard the trunk circuit 26 against seizure from the toll switchboard 30. At its contacts 728, the relay R120 connects the signal lead C642 to ground, thereby to energize the busy lamp as provided at each position of the toll switchboard 30. Thus the operators attending this switchboard are informed that the trunk circuit 26 and its associated trunk 5 are busy. At its contacts 721, the relay R120 completes a path through the contacts 751 for impressing ground potential upon the distributor start lead C723.

The supervisory relay R540, upon operating, opens its contacts 541 to interrupt the normally completed path including the contacts 631, C341 and C342, over which the terminating impedance comprising the resistor 344 and the condenser 345 is normally bridged across the talking leads connecting the two repeating coils 304 and 310. This "end termination" is normally provided to prevent voice current repeaters, which may be included in the connection in the toll office No. 1 and are set for high gain, from singing when the load impedance as measured between the conductors of the trunk 5 is suddenly changed. In operating, the relay R540 also closes its contacts 542 to prepare a locking circuit for itself. At its contacts 544, the relay R540 disconnects the signal lead C325 from ground. At its contacts 543, the relay R540 connects the signal lead C325 to the negative terminal of the exchange battery over a path which includes the contacts 575, 583, 613 and 543, and the resistor 601. When negative battery potential is substituted for ground potential upon the lead C325, the signal relay R320 remains in its operated position but the signal relay in the trunk circuit terminating the trunk 5 in the distant toll office No. 1 operates. In operating, the last-mentioned relay transmits a stop-in-dial or delay send signal to the register sender associated with the connection in the toll office No. 1 which indicates that the switching equipment in the called control office 10 is not ready to receive switch directing impulses. Operation of the register sender occupied with the call in the distant toll office No. 1 is delayed when this signal is received therein.

When the distributor start lead C723 is connected to ground in the manner explained above, the vertical position of the trunk 26d is marked in the banks of the finders to which this trunk is accessible. Also, the application of ground potential to this lead causes circuits to be set up in the distributor 39 and the finder 36 over which the selector 37 is seized and the finder is controlled to search for the calling trunk 26d. In

this regard it will be understood that the wipers 36a, 36b, 36c and 36d of the finder 36 are first operated vertically to a position opposite the marked level of bank contacts, after which they are rotated to a position wherein they engage the contacts terminating the conductors of the trunk 26d. When this trunk is found and the finder 36 switches through, the test wiper 36c thereof is connected to ground to energize the cut-off relay R150 in a circuit which includes the test conductor C177 and the contacts 722; a loop circuit is established between the trunk circuit 26 and the selector 37 over which the lower winding of the loop seizure relay R650 is energized in series with the two windings of the line relay R1320; and the E. C. conductor C1778 of the trunk 26d is connected to the E. C. lead C1338 of the selector 37. The manner in which the finder 36, as controlled by the distributor 39, operates to perform the functions just described is well understood in the art. Accordingly, the details of the finder 36 and the distributor 39 have been omitted from the disclosure.

When energized over the test lead C177, the cut-off relay R150 closes its contacts 752 to prepare a locking circuit for itself. At its contacts 751, the relay R150 disconnects the distributor start lead C723 from ground in the trunk circuit 26, whereby the link distributor 39 is operated in the usual manner to select another idle link for use in handling the next incoming trunk call.

As indicated above, the lower winding of the loop seizure relay R650 is energized in series with the two windings of the line relay R1320 incident to the switch-through operation of the finder 36. The circuit for energizing these two relays extends from ground by way of the lower winding of R1320, the contacts 1413, C1336, the wiper 36b, C776, the contacts 634, the repeating coil winding 314, the contacts 432, 631' and 661, the lower winding of R650, the contacts 633' and 434, the repeating coil winding 313, the contacts 632, C775, the wiper 36a, C1335, the contacts 1411, and the upper winding of R1320 to battery. When energized in this circuit, the relay R650 closes its contacts 653 to complete an obvious circuit for energizing the relay R740. At its contacts 652, the relay R650 opens a point in the circuit for energizing the two series-connected control relays R450 and R460. At its contacts 651, the relay R650 prepares a holding circuit for itself and also prepares the above-mentioned path for unbalancing the loop circuit established between the trunk circuit 26 and the selector 37.

The relay R740, upon operating, closes its contacts 741 to complete the locking circuit for the cut-off relay R150. At its contacts 742, the relay R740 completes the holding circuit for the loop seizure relay R650, this circuit extending from ground by way of the contacts 662, 742, 733, 724 and 651, the lower winding of R650, the contacts 633' and 434, the repeating coil winding 313, the contacts 632, C775, the wiper 36a, C1335, the contacts 1411, and the upper winding of R1320 to battery. It will be noted that when this holding circuit is completed, the lower winding of the line relay R1320 in the selector 37 is short-circuited. At its contacts 743, the relay R740 prepares the circuit for energizing the two control relays R450 and R460. At its contacts 745, the relay R740 opens the above-traced operating circuit for the supervisory relay R540. At its contacts 744, the relay R740 completes a locking circuit for itself, this circuit extending from ground by way of the

contacts 726, 423 and 744, and the winding of R740 to battery.

The supervisory relay R540, upon restoring, closes its contacts 541 to reconnect the terminating impedance 344, 345 across the talking conductors connecting the two repeating coils 304 and 310. At its contacts 542, the relay R540 opens the prepared holding circuit for itself. At its contacts 543 and 544, the relay R540 disconnects the signal lead C325 from the negative terminal of the exchange battery and reconnects this lead to ground. When ground potential is substituted for negative battery potential upon the signal lead C325, the signal relay in the trunk circuit terminating the trunk 5 in the toll office No. 1 releases to terminate the stop-in-dial signal which is being transmitted to the register sender associated with the connection in this toll office. Thus the indicated register sender is permitted to continue its operation, i. e., to transmit the remaining digits of the directory number designating the desired destination of the call.

The switch directing impulses as transmitted by the register sender in the distant toll office No. 1 to the trunk circuit terminating the trunk 5 in this office, are repeated by the pulsing relay of this trunk circuit as battery and ground pulses over the simplex of the trunk 5 to the signal relay R320. More specifically, the pulsing relay of the distant trunk circuit connects the two sides of the trunk 5 to ground during the open-circuit period of each impulse, and reconnects the two sides of this trunk to the negative terminal of the bakery in the office No. 1 during the closed-circuit period of each impulse. Each time the conductors of the trunk 5 are connected to ground, the signal relay R320 releases. Conversely, each time the conductors of this trunk are reconnected to the negative terminal of the battery in the office No. 1, the signal relay R320 reoperates. In opening and closing its contacts 321 the relay R320 repeats the impulses to the pulsing relay R660. The last-mentioned relay, upon releasing during the open-circuit period of each impulse, opens its contacts 661 and 662 to interrupt the previously traced operating and locking circuits for the two relays R650 and R1320. The operating circuit for these two relays is recompleted at the contacts 661 each time the pulsing relay R660 reoperates at the beginning of the closed-circuit period of a received impulse. Thus the impulses are repeated by the pulsing relay R660 to the selector 37. Each time the relay R660 restores to open its contacts 662, it also interrupts the operating circuit for the hold relay R710. Due to its slow-to-release characteristic, the hold relay R710 remains operated during impulsion.

Upon restoring at the beginning of the open-circuit period of the first impulse in each series of impulses, the relay R660 also closes its contacts 663 to complete the prepared operating circuit for the digit relay R730, this circuit extending from ground by way of the contacts 663, 432' and 712, and the winding of R730 to battery. It will be observed that this circuit is opened and closed at the contacts 663 as the pulsing relay R660 continues to follow the received impulses, and that it is held open during the inter-digit pause between succeeding digits transmitted to the trunk circuit 26. Since, however, the digit relay R730 is slow to release, it remains operated throughout each digit and only restores at the end of each digit. Each time this relay operates, it closes its contacts 731 to complete a path through the contacts 633' and 434 for shunting

the repeating coil winding 313 from the circuit over which the impulses are repeated to the selector 37. At its contacts 732, the relay R730 completes an obvious holding circuit for the loop seizure relay R650. In this regard, it is pointed out that the loop seizure relay is of the slow-to-release type and, accordingly, does not restore during the open-circuit period of the first impulse of each digit transmitted to the trunk circuit 26. At its contacts 733, the relay R730 opens another point in the previously traced holding circuit for the two relays R650 and R1320, and the path for short-circuiting the lower winding of the relay R1320. Each time the digit relay R730 restores at the end of a received digit, it opens its contacts 731 to again include the repeating coil winding 313 in the loop circuit connecting the trunk circuit 26 with the selector 37 or a succeeding selector and, at its contacts 732, interrupts the locking circuit for the loop seizure relay R650. At its contacts 733, the relay R730 recomplete the holding circuit for the loop seizure relay R650.

Seizing the selector 37

When the previously described loop circuit is completed between the trunk circuit 26 and the selector 37 to effect the energization of the line relay R1320, this relay closes its contacts 1321 to complete a circuit through the contacts 1411' for energizing the slow-acting hold relay R1330. At its contacts 1322, the relay R1320 opens a point in the circuit for transmitting impulses to the vertical magnet 1406 and the transfer relay R1400 in parallel. At its contacts 1323, the relay R1320 completes a path through the contacts 1521 and 1614 for impressing ground potential upon the in pulsing lead 35a extending to the register selector 38. The hold relay R1330, upon operating, closes its contacts 1331 to complete an obvious circuit for energizing the hold slave relay R1510. At its contacts 1332, the relay R1330 connects the two conductors C1337 and C1339 to ground, thereby to complete a circuit for holding the finder 36 operated; to complete a multiple circuit for energizing the cut-off relay R750; to prepare certain operating and locking circuits described hereinafter, and to complete a circuit through the vertical off-normal springs 1407 and the contacts 1333 for energizing the lower winding of the transfer relay R1400. At its contacts 1334, the relay R1330 prepares the circuit for energizing the vertical magnet 1406 in parallel with the upper winding of the transfer relay R1400. At its contacts 1335, the relay R1330 opens a point in the operating circuit for the release magnet 1310.

The relay R1400, upon operating, closes its contacts 1405 further to prepare the circuit for energizing the vertical magnet 1406 in parallel with its own winding. At its contacts 1402, the relay R1400 prepares a path for connecting the test wiper 1653 of the selector switching mechanism to ground. At its contacts 1401, the relay R1400 opens a point in the operating circuit for the test relay R1410. At its contacts 1403, the relay R1400 completes an obvious circuit for energizing the cut-in relay R1430. At its contacts 1404, the relay R1400 opens a point in the available circuits for energizing the local call relay R1440 and the relay R1630.

The hold slave relay R1510, in operating, closes its contacts 1511 to prepare the operating circuit for the test relay R1410 and, at its contacts 1512,

prepares a circuit for energizing the switching relay R1600. At its contacts 1513, the relay R1510 prepares the above-mentioned circuits for energizing the relays R1440 and R1630. At its contacts 1514, the relay R1510 opens a point in another of the available circuits for energizing the relay R1630. At its contacts 1515, the relay R1510 connects the control lead 35d to ground through the contacts 1635, thereby to complete the operating circuit for the line relay of the register selector 38.

The cut-in relay R1430, upon operating, closes its contacts 1434 to complete an obvious shunt across the pulsing contacts 1323 of the line relay R1320, thereby to prevent the impulses of the first digit transmitted to the selector 37 from being repeated through the register selector 38 to a seized register sender. At its contacts 1432, the relay R1430 completes an obvious path for short-circuiting the winding of the test relay R1410. At its contacts 1431 and 1433, the relay R1430 opens two points in the circuit for energizing the rotary magnet 1450.

When the control lead 35d is connected to ground, the register selector 38 operates to search for an idle register sender to which it has access. Assuming that the register sender 40 is seized through the outlet contacts of the register selector 38, the line relay thereof is energized in a circuit which includes the resistor 1324, the contacts 1323 and 1434 in parallel, the contacts 1527 and 1614, and the conductor 35a as connected through the register selector 38 to the register sender 40. In response to the operation of the line relay in the register sender 40, a locking circuit is completed for the line relay of the register selector 40 in order to hold this selector operated, and the control lead 35c is connected to ground. Incident to this operation, a circuit including the lead 35c and the contacts 1512 is completed for energizing the switching relay R1600.

The switching relay R1600, upon operating, locks to the control lead 35c through its contacts 1606 and, at its contacts 1605, opens a point in the circuit for energizing the switching relay R1520. At its contacts 1607, the relay R1600 completes an obvious circuit for energizing the relay R1630. At its contacts 1608, the relay R1600 opens a point in the operating circuit for the release magnet 1310. At its contacts 1604, the relay R1600 completes an obvious multiple path for impressing ground potential upon the release conductor C1339. At its contacts 1601 and 1603, the relay R1600 opens two points in the available but incomplete path for bridging one side of the repeating coil 1550 across the talking wipers 1651 and 1652 of the selector switching mechanism. At its contacts 1602, the relay R1600 prepares a circuit for energizing the relay R1620.

The relay R1630, upon operating, connects the test wiper 1653 to ground over a path which includes the contacts 1632 and 1402. At its contacts 1633, the relay R1630 prepares the operating circuit for the switching relay R1520. At its contacts 1634, the relay R1630 prepares its own locking circuit. At its contacts 1635, the relay R1630 disconnects the control lead 35d from ground, thereby to open the initially completed operating circuit for the line relay of the register selector 38.

Routing the call to a subscriber in the central office area

In considering the manner in which the call as

extended to the selector 37 is routed to its desired destination, it may first be assumed that the substation B is desired by the calling party and that the switches of the revertive pulse switch train 31 are utilized in extending the connection to this substation under the directive control of the digits transmitted from the toll office No. 1 to the trunk circuit 26 and repeated by this trunk circuit, first to the selector 37 and then to the register sender 40. The first digit transmitted to the trunk circuit 26 is utilized to direct the selector 37, in its operation to seize an idle first switch of the switch train 31. Thus when the line relay R1320 restores at the beginning of the open-circuit period of the first impulse of the first digit transmitted to the trunk circuit 26, it opens its contacts 1321 to interrupt the operating circuit for the hold relay R1330. At its contacts 1322, the relay R1320 completes the prepared circuit for energizing the vertical magnet 1406 in parallel with the upper winding of the transfer relay R1400, this circuit extending from ground by way of the contacts 1411', 1322, 1334 and 1405, and the parallel connected windings of the magnet 1406 and the relay R1400 to battery. It is noted that the opening of the contacts 1323, incident to the release of the line relay R1320, is of no effect since these contacts are shunted by the operated make contacts 1434 of the cut-in relay R1430. Accordingly, the impulses of the first digit transmitted to the trunk circuit 26 are not repeated to the register sender 40.

When energized in the circuit just traced, the vertical magnet 1406 operates to elevate the wipers 1651 to 1654, inclusive, one step wherein they are positioned opposite the first level of contacts in the associated contact field. When the line relay R1320 reoperates at the end of the open-circuit period of the impulse, it recloses its contacts 1321 to again energize the hold relay R1330, and opens its contacts 1322 to deenergize the vertical magnet 1406. During each succeeding impulse of the digit, the line relay R1320 operates to transmit a current pulse to the vertical magnet 1406, and this magnet responds by elevating the wipers of the selector 37 an additional step, so that at the end of the digit, these wipers are left standing in a position opposite the level of bank contacts at which are terminated the trunks of the revertive pulse selectors that are required to gain access to the desired substation B. Due to its slow-to-release characteristic, the hold relay R1330 remains operated during the impulsing.

Incident to the vertical movement of the wipers 1651 to 1654, inclusive, the off-normal springs 1407 are disengaged to interrupt the initially completed operating circuit for the transfer relay R1400. This relay, however, receives a current pulse through the break contacts 1322 of the line relay R1320 during the open-circuit period of each impulse of the first digit received in the selector 37, and due to its slow-to-release characteristic, remains operated throughout the digit. Also incident to the vertical off-normal movement of the wipers 1651 to 1654, inclusive, the off-normal springs 1408 are closed to complete the prepared locking circuit for the relay R1630; the off-normal springs 1314 are closed to prepare the operating circuit for the release magnet 1310; and the off-normal springs 1452 are closed to complete the prepared operating circuit for the step relay R1420, this circuit extending from the grounded release conductor C1339 by way of the

contacts 1417, 1432 and 1451, the off-normal springs 1452 and the winding of R1420.

When energized in the circuit just traced, the step relay R1420 locks to the grounded release conductor C1339 over a path which includes the off-normal springs 1452, the contacts 1451 and its preliminary make contacts 1422. At its contacts 1421, the relay R1420 prepares a circuit for energizing the rotary magnet 1450. In a call of the character under consideration, wherein the wipers 1651 to 1654, inclusive, are positioned opposite a level of bank contacts through which access is gained to the local automatic switching equipment of the central office, the normal post springs 1455 are disengaged and the normal post springs 1454 are moved into engagement in response to the indicated positioning of the selector wipers. At the normal post springs 1455, a point is opened in one of the circuits for energizing the relay R1630. At the normal post springs 1454, the operating circuit for the local call relay R1440 is prepared.

At the end of the first digit transmitted to the selector 37 and during the inter-digit pause between this and the succeeding digit, the line relay R1320 remains operated for a sufficient time interval to effect the release of the transfer relay R1400. This relay, upon restoring, opens its contacts 1402 to disconnect the test wiper 1653 from ground. At its contacts 1401, the relay R1400 prepares a circuit over which the test relay R1410 may be energized when the wipers of the selector 37 are rotated to engage a trunk extending to an idle selector in the local switch train. At its contacts 1403, the relay R1400 deenergizes the cut-in relay R1430. At its contacts 1404, the relay R1400 completes the prepared operating circuit for the local call relay R1440, this circuit extending from ground by way of the off-normal springs 1408, the contacts 1404 and 1513, the normal post springs 1454, and the winding of R1440 to battery. At its contacts 1405, the relay R1400 opens the above-traced circuit for energizing its own upper winding in parallel with the vertical magnet 1406. Thus the transfer relay R1400 and the vertical magnet 1406 are rendered non-responsive to further operation of the line relay R1320.

The local call relay R1440, upon operating, closes its contacts 1442 and 1446 to prepare the path for bridging one side of the repeating coil 1550 across the talking wipers 1651 and 1652. At its contacts 1443 and 1444, the relay R1440 shunts the contacts 1411 and 1413, respectively in order to continue the energization of the line relay R1320 and the loop seizure relay R650 after the test relay R1410 operates. At its contacts 1441 and 1445, the relay R1440 opens the paths for connecting the talking wipers 1651 and 1652 of the selector 37 directly to the talking wipers 36a and 36b of the finder 36. At its contacts 1447, the relay R1440 locks to the grounded release conductor C1339. At its contacts 1448, the relay R1440 closes another point in the operating circuit for the switching relay R1520. At its contacts 1449, the relay R1440 further prepares the operating circuit for the relay R1530. At its contacts 1441', the relay R1440 opens a point in the path for connecting the E. C. wiper 1654 of the selector 37 to the E. C. wiper 36d of the finder 36.

The cut-in relay R1430, upon restoring, opens its contacts 1432 to interrupt the path short-circuiting the test relay R1410. At its contacts 1431 and 1433, the relay R1430 completes the prepared operating circuit for the rotary magnet 1450, this circuit extending from the grounded release con-

ductor C1339 by way of the contacts 1417, 1433, 1421 and 1431, and the winding of the magnet 1450 to battery. At its contacts 1434, the relay R1430 opens the path shunting the pulsing contacts 1323 of the line relay R1320, thereby to render this line relay effective to repeat the impulses of additional received digits through the register selector 38 to the register sender 40 over the in pulsing lead 35a.

The rotary magnet 1450, upon operating, rotates the wipers 1651 to 1654, inclusive, into engagement with the contacts of the first contact set in the selected level, thereby to select the first local selector in the group corresponding to the selected level. In operating, the magnet 1450 also opens its contacts 1451 to deenergize the stepping relay R1420. The relay R1420 now restores and opens its contacts 1421 to deenergize the rotary magnet 1450. At its contacts 1422, the relay R1420 also opens the second completed path for short-circuiting the winding of the test relay R1410. When this path is opened the test relay R1410 is connected to be energized in the previously mentioned test circuit, which may now be traced as extending from the grounded release conductor C1339 by way of the winding of R1410, the contacts 1511, 1415, 1401 and 1632, and the wiper 1653 to the test conductor of the trunk extending to the selected switch. If the switch terminating this trunk is idle, the test conductor of the trunk is marked with negative battery potential to effect the energization and operation of the test relay R1410. In such case the relay R1410 operates to arrest the rotary movement of the selector wipers and to effect the seizure of the selected local selector in the manner explained below. On the other hand, if the selector terminating the first trunk of the group is busy, the test conductor thereof is marked with ground potential to prevent the operation of the test relay R1410. In such case, the stepping relay R1420, upon operating in response to the release of the rotary magnet 1450, closes its contacts 1421 to recomplete the operating circuit for the rotary magnet. This magnet, in reoperating, advances the wipers 1651 to 1654, inclusive, a second step in the rotary direction, whereby the trunk extending to the second selector of the selected group is selected for test. In operating, the magnet 1450 also deenergizes the stepping relay R1420. The interrelated operation of the magnet 1450 and the stepping relay R1420 continues until the wipers 1651 to 1654, inclusive, are positioned to engage the contacts terminating a trunk extending to an idle selector in the selected group, or until all of the trunks of the group have been tested and found busy.

Assuming that all of the selectors of the selected group are busy at the time the call is extended to the selector 37, the wipers 1651 to 1654, inclusive, are rotated to the eleventh rotary off-normal positions thereof. Incident to the eleventh rotary step of these wipers, the cam springs 1616 are disengaged, the cam springs 1617 are moved into engagement to energize the all-trunks-busy relay R1610, and the cam springs 1409 are moved into engagement to prepare an alternative circuit for energizing the transfer relay R1400.

The all-trunks-busy relay R1610, upon operating, closes its contacts 1611 to energize the switching relay R1520. At its contacts 1612, the relay R1610 prepares a path for transmitting ground pulses from the 120 I. P. M. lead C2637 over the E. C. conductor C1338 to the trunk cir-

cuit 26. At its contacts 1613, the relay R1610 opens the prepared path for impressing ground potential upon the E. C. lead C1338 and the E. C. wiper 1654. At its contacts 1614, the relay R1610 disconnects the control lead 35a from ground, whereby the register sender 40 and the register selector 38 are released. Incident to the release of these two control units the control lead 35c is disconnected from ground in the register sender 40 to effect the deenergization and release 10 of the switching relay R1600.

When the wipers 1651 to 1654, inclusive, are stepped to the eleventh rotary positions thereof, the test wiper 1653 is disconnected from ground to open one of the paths for short-circuiting the test relay R1410 and to open the circuit for directly energizing the stepping relay R1420. When the rotary magnet 1450 releases shortly thereafter, it closes a circuit for energizing the test relay R1410 and the stepping relay R1420 20 in series, this circuit extending from the grounded release conductor C1339 by way of the winding of R1410, the contacts 1451, the vertical off-normal springs 1452, and the winding of R1420 to battery. Due to the relatively high resistance of the winding of the test relay R1410, the stepping relay R1420 does not reoperate when energized in this circuit. The relay R1410, however, operates and closes its contacts 1418 to energize the lower winding of the transfer relay R1400 through the engaged cam springs 1409 and the contacts 1333. At its contacts 1411 and 1413, the relay R1410 opens two points in the loop circuit as initially established between the trunk circuit 26 and the selector 37. At its contacts 1412 and 1414, the relay R1410 prepares paths for connecting the talking lead C1335 and C1336 directly to the talking wipers 1651 and 1652. At its contacts 1415, the relay R1410 opens a point in the above-traced test circuit over which the test and stepping relays R1410 and R1420 are controlled. At its contacts 1417, the relay R1410 opens another point in the initially completed operating circuit for the rotary magnet 1450 and one of the paths for short-circuiting its own winding. At its contacts 1419, the relay R1410 further prepares the path for transmitting ground pulses from the pulsing lead C2637 over the E. C. lead C1338. At its contacts 1411', the relay R1410 opens the operating circuit for the hold relay R1330.

The switching relay R1520, upon operating, closes its contacts 1526 to complete an obvious circuit for energizing the relay R1540. At its contacts 1527, the relay R1520 opens another point in the path for connecting the in pulsing lead 35a to ground. At its contacts 1521 and 1524, the relay R1520 opens the paths shunting the contacts 1411 and 1413, respectively, of the test relay R1410. It will be noted in this regard that with both of the relays R1410 and R1520 operated, the line relay R1320 and the loop seizure relay R650 are deenergized. At its contacts 1522 and 1525, the relay R1520 further prepares the paths for connecting the talking wipers 36a and 36b of the finder 36 to one side of the repeating coil 1550. At its contacts 1523 and 1525, the relay R1520 completes a path which includes the resistor 1527, the winding 1533, and the contacts 1444 for impressing negative battery potential upon the talking conductor C1338.

The relay R1540, upon operating, closes its contacts 1541 to complete a path through the winding 1551 and the contacts 1522 and 1443 for 75

impressing negative battery potential upon the talking lead C1335. At its contacts 1543, the relay R1540 opens a point in the operating circuit for the relay R1520. At its contacts 1542, the relay R1540 completes the above-mentioned path for transmitting ground pulses from the 120 I. P. M. lead C2637 to the E. C. conductor C1338, this path also including the contacts 1612, 1627, 1449 and 1419.

The transfer relay R1400, upon reoperating, closes its contacts 1402 to connect the test wiper 1653 to ground and, at its contacts 1403, completes the operating circuit for the cut-in relay R1430. At its contacts 1404, the relay R1400 opens the operating circuit for the local call relay R1440. The cut-in relay R1430, upon reoperating, closes its contacts 1434 to shunt the pulsing contacts 1323 of the line relay R1320; closes its contacts 1432 to reprepare the path for shunting the test relay R1410; and, at its contacts 1431 and 1433, opens two additional points in the operating circuit for the rotary magnet 1450. The line relay R1320, upon restoring, opens its contacts 1321 further to interrupt the operating circuit for the hold relay R1330, and, at its contacts 1322, reprepares the circuit for energizing the vertical magnet 1406 in parallel with the upper winding of the transfer relay R1400.

As indicated above, when the register sender 30 and the register selector 38 are released, the control lead 35c is disconnected from ground to deenergize the switching relay R1600. This relay, upon restoring, opens its contacts 1604 to interrupt one of the multiple paths over which 35 the release conductor C1339 is connected to ground. At its contacts 1607, the relay R1600 opens the operating circuit for the relay R1630. At its contacts 1605, the relay R1600 completes an obvious multiple circuit for energizing the 40 switching relay R1520. At its contacts 1608, the relay R1600 prepares the operating circuit for the release magnet 1310.

The hold relay R1330, upon restoring, opens its contacts 1331 to deenergize the hold slave relay 45 R1510. At its contacts 1332, the relay R1330 disconnects the release conductor C1339 from ground in the selector 37. It is noted, however, that this conductor is now connected to ground in the trunk circuit 26 over a path which includes the test wiper 36c, the test conductor C777 and the contacts 722, 752 and 741. Accordingly, the relays R1410 and R1440 are prevented from 50 releasing in response to the release of the hold relay R1330. At its contacts 1333, the relay R1330 deenergizes the transfer relay R1400.

The hold slave relay R1510, upon restoring, opens its contacts 1511 further to interrupt the previously traced trunk test circuit and, at its contacts 1512, opens a point in the operating 60 circuit for the switching relay R1600. At its contacts 1513, the relay R1510 opens another point in the operating circuit for the local call relay R1440. At its contacts 1514, the relay R1510 prepares a multiple E. C. path through the selector 37. At its contacts 1515, the relay R1510 opens 65 another point in the path for connecting the register control lead 35d to ground.

The transfer relay R1400, upon restoring, opens its contacts 1403 to deenergize the cut-in relay R1430. Otherwise the release of the transfer relay R1400 is without effect. The release of the cut-in relay R1430 is likewise without effect. Following the release of the two relays R1400 and R1430, no further relay operations occur in the 70 selector 37 until such time as the trunk circuit

26 is released under the control of the calling operator. In this regard, it will be noted that when an all-trunks-busy condition is encountered in the selector 37, the relays R1410, R1440, R1520, R1540, R1310 and R1630 are energized therein until such time as the preceding trunk circuit is released.

When the loop connecting the trunk circuit 26 and the selector 37 is opened at the contacts of the two relays R1410 and R1520 in the manner explained above, the loop seizure relay R650 of the trunk circuit 26 is deenergized and restores. In releasing, this relay opens its contacts 651 further to interrupt the previously traced holding circuit for itself and the line relay R1320. At its contacts 653, the relay R650 opens the operating circuit for the relay R740. At its contacts 652, the relay R650 completes the prepared circuit for energizing the two relays R450 and R460 in series, this circuit extending from ground by way of the contacts 439, 743 and 652, and the series connected windings of the two relays R460 and R450 to battery. When energized in this circuit both of the control relays R450 and R460 operate. In operating, the relay R450 closes its contacts 451 to complete an obvious circuit for energizing the switching relay R440. The relay R460, upon operating, closes its contacts 461 to prepare the operating circuit for the switching relay R430 and, at its contacts 462, completes an obvious circuit for energizing the control relay R470.

The switching relay R440, upon operating, locks to ground over a path which includes the contacts 449 and 725. At its contacts 448, the relay R440 opens a point in one of the available paths for impressing ground potential upon the E. C. lead C780. At its contacts 447, the relay R440 prepares an alternative path for connecting the E. C. lead C780 to ground in the trunk circuit 26. At its contacts 445, the relay R440 disconnects the E. C. lead C778 from the winding of the transfer relay R550. At its contacts 446, the relay R440 completes a circuit including the E. C. lead C778 for transmitting the ground pulses applied to the impulsive lead C2631 through the upper winding of the supervisory relay R540. This circuit may now be traced as extending from the impulsive lead C2631 by way of the contacts 1612, 1627, 1542, 1449 and 1418, C1338, the wiper 36d, C788, the contacts 448, and the upper winding of R540 to battery. When this circuit is completed the supervisory relay R540 is rendered effective to follow the ground pulses transmitted over the impulsive lead C2631. At its contacts 444, the relay R440 opens a point in the holding circuit for the loop pulsing relay R610. At its contacts 441 and 443, the relay R440 prepares a path for short-circuiting the condenser 331 connected between the inner terminals of the repeating coil windings 313 and 314. At its contacts 442, the relay R440 opens a point in the operating circuit for the rering relay R480.

The relay R470, upon operating, closes its contacts 474 to prepare the locking circuit for the supervisory relay R540. At its contacts 472, the relay R470 opens the path for short-circuiting the condenser 331. At its contacts 471, the relay R470 prepares a locking circuit for the relay R570. At its contacts 473, the relay R470 completes the prepared operating circuit for the switching relay R430.

The relay R430 now operates and closes its contacts 431 and 433, further to prepare the

path for short-circuiting the condenser 331. At its contacts 432 and 434, the relay R430 opens two additional points in the loop circuit as initially completed between the selector 37 and the trunk circuit 26. Thus it will be noted that at the contacts 433 and 434 the upper talking lead C775 is open-circuited in the trunk circuit 26 when the switching relay R430 operates. At its contacts 435, the relay R430 prepares the holding circuit for the loop pulsing relay R610. At its contacts 437, the relay R430 opens a point in the available path for impressing negative battery potential upon the E. C. lead C780. At its contacts 438, the relay R430 prepares one of the paths over which ground potential may be impressed upon this E. C. lead. At its contacts 431', the relay R430 locks to ground through the contacts 725. At its contacts 439, the relay R430 deenergizes the two control relays R450 and R460. At its contacts 432', the relay R430 opens a point in the incomplete operating circuit for the digit relay R130. At its contacts 436, the relay R430 opens a point in the operating circuit for the loop pulse relay R610. At its contacts 431, the relay R430 also completes a circuit for energizing the simplex pulse relay R680 in series with the resistor 1527 of the selector 37. This circuit as initially completed extends from ground by way of the contacts 321 and 638, the winding of R680, the contacts 636, 441 and 431, the repeating coil winding 314, the contacts 634, C776, the wiper 36b, C1336, the contacts 1444 and 1525, the repeating coil winding 1553, the contacts 1523, and the resistor 1527 to battery.

The relay R450, upon restoring, opens its contacts 451 to interrupt the operating circuit for the switching relay R440. The other control relay R460, in releasing, opens its contacts 461 to interrupt the operating circuit for the switching relay R430 and, at its contacts 462, deenergizes the control relay R470. The relay R470 now restores and opens its contacts 474 to interrupt the locking circuit for the supervisory relay R540. At its contacts 473, the relay R470 opens another point in the operating circuit for the switching relay R430. At its contacts 412, the relay R470 short-circuits the condenser 331 through the contacts 431, 441, 433 and 443, and in so doing completes the other branch of the simplex circuit for energizing the simplex relay R680. This branch circuit may be traced as extending from ground by way of the contacts 321 and 638, the winding of R680, the contacts 636, 472, 443 and 433, the repeating coil winding 313, the contacts 632, C775, the wiper 36a, C1335, the contacts 1443 and 1522, the repeating coil winding 1551, the contacts 1541, and the resistor 1527 to battery. It will be noted that this simplex circuit is controlled by the contacts 321 of the signal relay R320, so that any further impulses transmitted to the trunk circuit 26 from the distant toll office No. 1 are followed by the simplex relay R680. Such impulses have no effect however upon the setting of the selector 37.

The simplex relay R680 operates when energized in the above-traced simplex circuit, and closes its contacts 681 to complete an obvious circuit for energizing the slow-acting simplex slave relay R670. The simplex slave relay R670, upon operating, opens its contacts 671 to deenergize the pulsing relay R660 and, at its contacts 672, completes a holding circuit for the hold relay R710. The pulsing relay R660 now restores and opens its contacts 662 to interrupt the operating

circuit for the hold relay R710. At its contacts 661, the relay R660 opens a point in the initially completed path for bridging the operating winding of the loop seizure relay R650 across the talking conductors C115 and C178. At its contacts 663, the relay R660 prepares the previously traced operating circuit for the digit relay R730.

The supervisory relay R540, in following the ground pulses transmitted to the trunk circuit 26 from the selector 37 over the E. C. lead C178, alternately connects the signal lead C325 to ground and to the negative terminal of the exchange battery. Thus the pulses which are transmitted to the supervisory relay R540 at the rate of 120 pulses per minute are repeated over the simplex circuit of the trunk 5 to the signal relay in the trunk circuit terminating this trunk in the toll office No. 1. This signal relay, in following the ground and battery pulses applied to the signal lead C325, causes a supervisory lamp associated with the connection at the toll switchboard in this office to flash and inform the originating operator that an all-busy switching stage has been reached in the central office 10, beyond which the connection cannot be extended. Upon receiving this signal, the originating operator may release the connection as extended to the selector 37 in the manner pointed out below.

Assuming now that the wipers 1651 to 1654, inclusive, are operated to engage the contacts terminating the conductors of a trunk extending to an idle local selector during the rotary movement thereof, it will be understood that ground potential is removed from the test wiper 1653 when the idle local selector is found. When this wiper is disconnected from ground, no further circuit is available for fully energizing the stepping relay R1420. Accordingly, this relay remains in its restored position to prevent further energization of the rotary magnet 1450. Thus the rotary movement of the wipers 1651 to 1654 is arrested. The rotary magnet 1450, upon restoring, following the last step imparted to the enumerated wipers, closes its contacts 1451 to energize the test relay R1410 and the stepping relay R1420 in series over the circuit traced above. Only the test relay R1410 operates when energized in this circuit. In this case, the test relay R1410, in closing its contacts 1418, only prepares the operating circuit for the transfer relay R1400, this circuit being held open at the cam springs 1409. At its contacts 1411', the relay R1410 opens the operating circuit for the hold relay R1330. At its contacts 1419, the relay R1410 completes the prepared operating circuit for the relay R1530, this circuit extending from ground by way of the winding of R550, the contacts 445, the E. C. lead C178, the wiper 36d, C1338, the contacts 1419, 1449 and 1543, and the winding of R1530 to battery. Since the winding of the relay R1530 is of relatively high resistance, the transfer relay R550 does not operate when energized in this circuit. At its contacts 1416, the relay R1410 connects the test wiper 1653 to ground over a path which includes the cam springs 1616 and the contacts 1401 and 1632. The remaining circuit switching operations performed by the test relay R1410 are the same as described above.

The relay R1530 operates when energized in the above-traced series circuit and, at its contacts 1531, opens a point in the operating circuit for the relay R1540. The hold relay R1330, upon restoring, opens its contacts 1332 to interrupt one of the multiple paths over which the release con-

ductor C1339 is connected to ground in the selector 37. At its contacts 1331, the relay R1330 deenergizes the hold slave relay R1510. At its contacts 1335, the relay R1330 further prepares the operating circuit for the release magnet 1310. At its contacts 1333, the relay R1330 opens a point in the operating circuit for the transfer relay R1400. At its contacts 1334, the relay R1330 opens another point in the circuit for energizing the vertical magnet 1406 in parallel with the upper winding of the transfer relay R1400.

The hold slave relay R1510, upon restoring, opens its contacts 1511 further to interrupt the previously traced trunk test circuit and, at its contacts 1512, opens the previously traced operating circuit for the switching relay R1600. At its contacts 1513, the relay R1510 opens the operating circuit for the local call relay R1440. At its contacts 1514, the relay R1510 prepares an E. C. control path through the selector 37. At its contacts 1515, the relay R1510 opens another point in the path for impressing ground potential upon the register control lead 35d. Following the release of the hold slave relay R1510 the selector 37 is conditioned to repeat the impulses of the remaining digits of the directory number designating the desired substation B through the register selector 38 to the register sender 40. In this regard it will be noted that the relays R1320, R1410, R1440, R1530, R1600 and R1630 are operated in the selector 37 after it has been shifted to its impulse repeating setting.

The line relay R1320 follows the impulses transmitted to the trunk circuit 26 from the distant toll office No. 1 and repeated to the selector 37 through the contacts 321 of the signal relay R320. These impulses are repeated through the pulsing contacts of the line relay R1320 to the register sender 40 over the in pulsing lead 35a. The opening and closing of the contacts 1321 and 1322 during the impulse repeating operation of the line relay R1320 is of no effect.

By reference to the previously cited Peterson et al. Patent No. 2,341,879, wherein the details of the register selector 38 and the register sender 40 are disclosed, it will be understood that the digits registered in the register sender 40 during the impulse repeating operation of the line relay R1320 are retransmitted over the out pulsing lead 35b under the revertive control of the automatic switches in the switch train 31. More specifically, the impulses of the registered digits are transmitted to the switches of the revertive pulse switch train 31 over a path which includes the out pulsing lead 35b, the contacts 1446, and the positive talking wiper 1652. The impulses of these digits are utilized to direct the connection through the switch train 31 to the substation B in a manner well understood in the art.

When the register sender 40 has been cleared of all digits registered therein, it releases, and disconnects the control lead 35c from ground to effect the release of the switching relay R1600 and the register selector 38, in the manner explained in the Peterson et al. Patent No. 2,341,879, cited above. Incident to the release of the register sender 40 and the register selector 38, the out pulsing circuit including the lead 35b is interrupted, leaving this lead open-circuited in the register selector 38. The switching relay R1600, upon restoring, closes its contacts 1601 and 1603 to reprepare the path for bridging the two windings 1555 and 1558 of the repeating coil 1550 across the talking wipers 1651 and 1652 in series with the windings of the answer relay R1560 and

the exchange battery. At its contacts 1602, the relay R1600 opens a point in the prepared operating circuit for the relay R1520. At its contacts 1604, the relay R1600 disconnects the release conductor C1339 from ground in the selector 37, thereby to render the release of this selector controllable from the preceding trunk circuit 26. At its contacts 1605, the relay R1600 completes the previously traced operating circuit for the switching relay R1520. At its contacts 1606, the relay R1600 opens a point in its own locking circuit. At its contacts 1607, the relay R1600 opens the operating circuit for the relay R1530. At its contacts 1608, the relay R1600 prepares the operating circuit for the release magnet 1310.

The switching relay R1520, upon operating, opens its contacts 1521 and 1524 to deenergize the line relay R1320 and the loop seizure relay R650 in the manner explained above. At its contacts 1522 and 1525, the relay R1520 bridges the repeating coil windings 1551 and 1553 across the talking wipers 36a and 36b of the finder 36 in series with the condenser 1554. At its contacts 1523 and 1525, the relay R1520 connects the negative terminal of the exchange battery to the talking wiper 36b over a path which includes the resistor 1527, the winding 1553, and the contacts 1444. At its contacts 1526, the relay R1520 prepares the operating circuit for the relay R1540. At its contacts 1527, the relay R1520 disconnects the in pulsing lead 35a from ground in the selector 37. The line relay R1320, upon restoring, performs the functions described above.

When the loop circuit connecting the selector 37 with the trunk circuit 26 is opened at the contacts 1521 and 1524 in the manner just described, the loop seizure relay R650 is deenergized and restores. In releasing, this relay effects the operation of the relays R460, R450, R470, R440, R430, R680 and R670, followed by the release of the relays R450, R460 and R660, in the exact manner explained above with reference to the all-trunks-busy condition encountered in the selector 37. In this case, however, the switching relay R440, in opening its contacts 445, interrupts the previously traced operating circuit for the relay R1530. At its contacts 446, the relay R440 prepares the circuit for controlling the supervisory relay R540 over the E. C. conductor C778 from the selector 37. In this regard it will be noted that after the switching relay R440 operates, the upper winding of the relay R540 is shunted by the winding of the relay R1530.

The relay R1530, upon restoring, closes its contacts 1531 to complete the operating circuit for the relay R1540. The later relay, upon operating, opens its contacts 1543 further to interrupt the operating circuit for the relay R1530 and, at its contacts 1542, prepares a path for connecting the E. C. conductor C778 to ground in the selector 37. At its contacts 1541 the relay R1540 completes the second branch of the simplex circuit extending between the selector 37 and the trunk circuit 26. Following the operations just described, and during the period required to signal the called substation B in the line switch of the train 31, no further operations occur in the selector 37 or the trunk circuit 26.

When the call is answered at the called substation B, the talking wipers 1651 and 1652 are conductively inter-connected to provide a circuit through the contacts 1442, 1446, 1601 and 1603 for energizing the windings of the answer relay R1560. This relay, in operating, opens its contacts 1561 to interrupt the path over which the

terminating impedance 1563, 1564 is normally bridged across the line terminals of the repeating coil windings 1551 and 1553. At its contacts 1562, the relay R1560 connects the E. C. leads C1338 and C778 to ground, thereby to provide a circuit for energizing the upper winding of the supervisory relay R540. More specifically, this circuit extends from ground by way of the contacts 1562, 1613, 1542, 1449 and 1419, C1338, the wiper 36d, C778, the contacts 446, and the upper winding of R540 to battery. When thus energized, the relay R540 substitutes negative battery potential for ground potential upon the signal lead C325, whereby the supervisory lamp associated with the trunk 5 in the distant manual office No. 1 is controlled to provide the usual off-hook supervisory signal. In this regard it will be understood that after the call is answered at the called substation B, the desired talking circuit is completed between this substation and the calling operator in the distant toll office No. 1. Accordingly this operator may extend the connection to the calling substation through the line connecting facilities of the toll switchboard in this office. It is noted that after the call is answered at the called substation, talking battery is supplied to the telephone instrument at this substation through the windings of the answer relay R1560.

With the illustrated arrangement, the answer relay R1560 may be controlled from the called substation B to transmit switchhook supervision to the distant toll office No. 1. Thus each time the switchhook provided at this substation is operated to open the conductive connection between the talking wipers 1651 and 1652, the relay R1560 restores and opens its contacts 1562 to deenergize the supervisory relay R540. This relay, in releasing, substitutes ground potential for negative battery potential on the signal lead C325, whereby an on-hook supervisory signal is produced by the supervisory lamp associated with the trunk 5 in the distant toll office No. 1. Conversely, each time the switchhook at the called substation B is operated to recomplete the conductive connection between the talking wipers 1651 and 1652, the answer relay R1560 reoperates to recomplete the operating circuit for the supervisory relay R540 and thus effect the transmission of an off-hook supervisory signal to the distant toll office. It will also be understood that when the called subscriber disconnects, the answer relay R1560 and the supervisory relay R540 are sequentially released and remain in their respective restored positions. Accordingly, a steady on-hook supervisory signal is produced by the supervisory lamp associated with the trunk 5 in the distant toll office.

If, in the extension of the connection through the switch train 31, an all-trunks-busy condition is encountered at a predetermined switching stage, the last switch to which the call is extended operates to transmit a relatively long ground pulse over the positive side of the connection. When the wiper 1651 is thus connected to ground, a circuit including this wiper and the contacts 1442, 1602 and 1621 is completed for energizing the all-trunks-busy relay R1620. This relay, upon operating, locks to the grounded release conductor C1339 through its preliminary make contacts 1624. After completing this locking circuit, the relay R1620 opens its contacts 1621 to interrupt its operating circuit. At its contacts 1622, the relay R1620 completes the operating circuit for the busy relay R1640, this

circuit extending from the grounded wiper 1651 by way of the contacts 1442, 1602 and 1622 and the winding of R1640 to battery.

In operating, the relay R1620 also opens its contacts 1623 to interrupt the circuit for energizing the answer relay R1560. At its contacts 1625, the relay R1620 completes an obvious circuit for energizing the all-trunks-busy relay R1610. At its contacts 1626, the relay R1620 prepares a path for transmitting ground pulses over the E. C. leads C1338 and C1718 to the trunk circuit 26. At its contacts 1627, the relay R1620 opens the previously traced path including the 120 I. P. M. lead C2637 for transmitting ground pulses over the two enumerated E. C. leads.

The busy relay R1640, in operating, locks to the grounded release conductor C1339 through its contacts 1641. At its contacts 1643, the relay R1640 opens the available path for transmitting ground pulses over the E. C. lead C1338 from the 60 I. P. M. lead C2638. At its contacts 1642, the relay R1640 prepares an alternative path for transmitting ground pulses over the E. C. lead C1338 from the 120 I. P. M. lead C2637.

The all-trunks-busy relay R1610, upon operating, closes its contacts 1611 to energize the switching relay R1520. At its contacts 1614, the relay R1610 disconnects the in pulsing lead 35a from the pulsing contacts 1323, thereby to prevent further impulses from being transmitted to the register sender 40. When the impulsive circuit is thus opened, the register sender 40 and the selector 38 are released in the manner explained in the above-referred to copending application of Peterson et al. Incident to the release of these two units, the holding circuit for the switching relay R1600 is opened, causing this relay to restore.

The switching relay R1520, upon operating, prepares the operating circuit for the relay R1540, and opens its contacts 1521 and 1524 to deenergize the line relay R1320 and the loop seizure relay R650. At its contacts 1523, the relay R1520 prepares one side of the simplex circuit over which the simplex relay R680 may be energized.

When the loop seizure relay R650 restores it effects the operation of the relays R430, R440, R450, R460, R680 and R670 and the deenergization of the relay R1530 in the exact manner explained above. The relay R1530, upon restoring, closes the operating circuit for the relay R1540. The latter relay, upon operating, closes its contacts 1542 to complete the prepared alternative path for transmitting ground pulses over the connected E. C. leads C1338 and C1718 to the supervisory relay R540 of the trunk circuit 26. This path, as completed between the E. C. lead C1338 and the 120 I. P. M. lead C2637, includes the contacts 1419, 1449, 1542, 1626 and 1642. When this path is completed, the supervisory relay R540 functions to repeat the busy flash signal over the toll trunk 5 to the distant toll office No. 1 in the exact manner explained above. In this regard it is noted that the rate of flashing of the supervisory lamp associated with the trunk 5 in the distant toll office, i. e., 120 flashes per minute, serves to inform the operator handling the call in this office that the connection has been extended to a blocked switching stage.

If the called line extending to the substation B is occupied with a call at the time the connection is extended thereto through the switch train 31, this line tests busy to the last switch in the train. In such case the control equipment in the last

switch of the train operates to transmit an exceedingly short ground pulse over the positive side of the connection. This ground pulse effects the operation of the all-trunks-busy relay R1620 in the exact manner explained above but does not persist for a sufficient interval of time to cause the operation of the slow-to-operate busy relay R1640. The relay R1620, upon operating, causes a flash busy signal to be transmitted through the trunk circuit 26 to the operator handling the call in the distant toll office No. 1 in a manner which will be clearly apparent from the above explanation. In this case, however, the supervisory relay R540 is controlled through the break contacts 1643 in accordance with the ground pulses transmitted over the 60 I. P. M. lead C2638. Accordingly, the supervisory lamp associated with the trunk 5 in the distant toll office is flashed at a much lower rate to inform the operator handling the call that the connection has been extended as far as the called line but that this line is busy.

The operator handling the call in the toll office No. 1 upon receiving the steady on-hook supervisory signal in the manner explained above, may release the connection by effecting the key or relay operations which are required to disconnect the two sides of the trunk 5 from the negative terminal of the battery in this toll office. In response to this operation, the signal relay R320 restores and opens its contacts 321 to deenergize the simplex relay R680. The relay R680, upon restoring, opens its contacts 681 to deenergize the simplex slave relay R670. The latter relay, in releasing, opens its contacts 672 to deenergize the hold relay R710.

The hold relay R710, upon restoring, opens its contacts 711 to deenergize the hold slave relay R720. At its contacts 712, the relay R710 opens a point in the previously traced operating circuit for the digit relay R730. The hold slave relay R720 now restores and opens its contacts 722 to disconnect the test conductor C711 from ground in the trunk circuit 26. At its contacts 721, the relay R720 opens a point in the path for connecting the distributor start lead C723 to ground in the trunk circuit 26. At its contacts 723, the relay R720 disconnects the test conductor C719 from ground. At its contacts 724, the relay R720 prepares the operating circuit for the seizure relay R640 and applies negative battery potential to the test lead C719. Thus the trunk circuit 26 is marked as idle in the bank contacts of the selectors to which it is accessible. At its contacts 725, the relay R720 opens the locking circuits for the two switching relays R430 and R440. At its contacts 726, the relay R720 opens the locking circuit for the relay R740. At its contacts 727, the relay R720 reprepares the operating circuit for the seizure relay R760. At its contacts 728, the relay R720 disconnects the signal lead C642 from ground, thereby to deenergize the signal lamp as provided at each position of the toll switchboard 30. The deenergization of these signal lamps serves to inform the operators attending the switchboard 30 that the trunk circuit 26 is idle. The release of the two switching relays R430 and R440 is without effect. The relay R740, upon restoring, opens its contacts 741 to deenergize the cut-off relay R758. Following the release of the latter relay the trunk circuit 26 is fully restored to normal and may be seized over any one of its four points of access.

As pointed out above, the connected conductors C711, C1337 and C1338 are disconnected from ground in response to the release of the hold

slave relay R120 in the trunk circuit 26. When the conductor C1337 is disconnected from ground the finder 36 is released in a manner well understood in the art. When the release conductor C1339 is disconnected from ground, the relays R1410 and R1440 and the relays R1620 and R1640, if operated, are deenergized and restore. The relay R1440, upon restoring, opens its contacts 1448 to deenergize the switching relay R1520. The latter relay, in restoring, opens its contacts 1526 to effect the deenergization and release of the relay R1540.

The test relay R1410, upon restoring, opens its contacts 1416 to disconnect the test wiper 1653 from ground, thereby to initiate the release of the switches in the train 31 in a manner well understood in the art. At its contacts 1411', the relay R1410 completes the prepared operating circuit for the release magnet 1310, this circuit extending from ground by way of the contacts 1411', 1322, 1335 and 1608, the off-normal springs 1314 and the winding of the magnet 1310 to battery. When thus energized, the magnet 1310 attracts its associated holding pawl to permit the wipers 1651 to 1654, inclusive, to be returned to rotary and vertical normal in the usual manner. Incident to the release of these wipers the normal post springs 1454 are opened further to interrupt the operating circuit for the relay R1440; the normal post springs 1455 are closed to prepare the circuit for energizing the relay R1630; the off-normal springs 1314 are opened to deenergize the release magnet 1310; the off-normal springs 1408 are opened to deenergize the relay R1630; the off-normal springs 1407 are closed to reprepare the operating circuit for the transfer relay R1400; and the off-normal springs 1452 are opened further to interrupt the operating circuit for the stepping relay R1420 and the circuit for energizing the test relay R1410. It may be noted that if the connection is released after an all-trunks-busy or line busy condition is encountered in the selector 37 or a succeeding selector, the cam springs 1617 or the contacts 1625 are opened to deenergize the all-trunks-busy relay R1610 incident to the release of the wipers 1651 to 1654, inclusive. Following the release of the magnet 1310, the relay R1630, and the relay R1610, if operated, the selector 37 is fully restored to normal. In this regard it is pointed out that during the interval when the release magnet 1310 is operated, the conductor C1337 is connected to ground through the contacts 1311, thereby to provide a path for guarding the link 35 against distribution by the link distributor 39. This path is opened at the contacts 1311 to render the link 35 assignable by the distributor 39 in response to the release of the magnet 1310.

Routing the call to the manual office

If the above-described call originating in the toll office No. 1 and routed through the trunk circuit 26 to the link 35 is to be extended through the inter-toll dial train to the manual office No. 1, the calling operator in the toll office No. 1 may dial or key up the digits assigned to the group of trunks connecting the central office 10 with the manual office No. 1. When the first of these digits is transmitted to the selector 37 through the trunk circuit 26 in the manner previously explained, the wipers of this selector are elevated to a position opposite the level of bank contacts in which the trunks of the group including the trunk 32d, are terminated. On a call of this character, i. e., one which is not to be extended

through the local automatic switching equipment in the central office, the normal post springs 1454 and 1455 are not operated at the end of the vertical movement of the selector switch wipers. Accordingly the operating circuit for the local call relay R1440 is not completed at the contacts 1404 in response to the release of the transfer relay R1400 at the end of the first digit transmitted to the selector 37.

- 10 The transfer relay R1400, upon restoring, initiates the automatic trunk hunting operation of the selector 37 in the exact manner previously explained. In the event all of the trunks of the selected group are busy at the time the call is extended to the selector 37, a flash busy supervisory signal is transmitted through the trunk circuit 26 and over the trunk 5 to the distant toll office No. 1 in the manner pointed out above. On the other hand, if an idle trunk is found during the trunk hunting operation, the test relay R1410 is energized and operates to perform its assigned functions immediately the wipers 1651 to 1654 are positioned on the contacts terminating the conductors of the idle trunk. For purposes of explanation, it may be assumed that the toll selector 32 is seized during the trunk hunting operation of the selector 37. In this regard it will be noted that with the local call relay R1440 deenergized, the test relay R1410, upon operating, closes its contacts 1412 and 1414 to extend the loop circuit as completed between the selector 37 and the trunk circuit 26 to the toll selector 32. In operating, the test relay R1410 also opens its contacts 1411' to deenergize the hold relay R1330. At its contacts 1411 and 1413, the relay R1410 deenergizes the line relay R1320. At its contacts 1416, the relay R1410 completes a previously traced path for connecting the test wiper 1653 to ground in the selector 37. Thus the relay R1410, upon operating, causes the sequential release of the three relays R1320, R1330 and R1510 in the selector 37. The relay R1320, upon restoring, opens its contacts 1323 to disconnect the in pulsing lead 35a from ground and thus effect the release of the register sender 40, the register selector 38 and the switching relay R1600 in the manner previously explained. With the test relay R1410 operated and the local call relay R1440 in its restored position, a path is completed through the contacts 1419 and 1441' and the wiper 1654 for connecting the E. C. leads C178 and C1338 to the E. C. lead C1706 of the trunk 32d. Thus a path is prepared for transmitting supervisory signals from the toll selector 32 through the toll selector 37 to the trunk circuit 26. It will be noted that after the switch-through operation is effected in the selector 37 in the manner explained above, only the relays R1410 and R1630 are operated in this selector.
- 60 When the selector 37 switches through in the manner explained above, the line relay R1730 is energized in the loop circuit which may now be traced as extending from ground by way of the cam springs 1616, the contacts 1416, 1401 and 1632, the wiper 1653, C1705, the lower winding of R1730, the contacts 1723, C1704, the wiper 1652, the contacts 1445 and 1414, C1336, the wiper 36b, C1716, the contacts 634, the repeating coil winding 314, the contacts 432, 631' and 661, the lower winding of R650, the contacts 633' and 434, the repeating coil winding 313, the contacts 632, C1715, the wiper 36a, C1335, the contacts 1412 and 1441, the wiper 1651, C1703, the contacts 1721 and the upper winding of R1730 to battery. Also incident to the switch-through operation of the
- 65
- 70
- 75

selector 37, the transfer relay R1810 is energized in a circuit which extends from the grounded test lead C1705 by way of the off-normal springs 1801 and the lower winding of R1810 to battery. When energized in the above-traced loop circuit, 5 the line relay R1730 closes its contacts 1731 to complete a circuit through the contacts 1725 for energizing the slow-acting hold relay R1740. At its contacts 1732, the relay R1730 opens a point in the circuits for energizing the release magnet 1748, the vertical magnet 1817, the upper winding of the transfer relay R1810, the transfer relay R1830 and the rotary magnet 1870. At its contacts 10 1733, the relay R1730 prepares the operating circuit for the rotary magnet 2041 of the minor switch 2040.

The transfer relay R1810, upon operating, closes its contacts 1811 to complete a circuit including the grounded test conductor C1705 and the normal post springs 1803 for energizing the transfer 20 relay R1820. At its contacts 1812, the relay R1810 prepares a circuit for energizing the vertical magnet 1817 in parallel with its own upper winding. At its contacts 1813, the relay R1810 opens a point in the operating circuit for the 25 transfer relay R1830. At its contacts 1814, the relay R1810 opens a point in the circuit for energizing the rotary magnet 1870 and the transfer relay R1830 in parallel. At its contacts 1815, the relay R1810 prepares a path for impressing 30 ground potential upon the test wiper 2053. At its contacts 1816, the relay R1810 opens a point in the test circuit over which the test relay R1700 may be energized.

The hold relay R1740, upon operating, closes its contacts 1741 to connect the test conductor C1705 to ground in the selector 32. At its contacts 1742, the relay R1740 further prepares the circuit for energizing the vertical magnet in parallel with the upper winding of the transfer relay R1810. At its contacts 1743, the relay R1740 opens a point in the operating circuit for the release magnet 1748. At its contacts 1744, the relay R1740 prepares a circuit for energizing the rotary magnet 1870 and the transfer relay R1830 in parallel. At its contacts 1745, the relay R1740 prepares the test circuit over which the test relay R1700 may be energized.

The transfer relay R1820, upon operating, closes its contacts 1821 to prepare a locking circuit for the relay R1860. At its contacts 1822, the relay R1820 locks to the grounded conductor C1705 over a path which includes the contacts 1822 and the normal post springs 1803. At its contacts 1823, the relay R1820 prepares the circuit for energizing the transfer relay R1830 in parallel with the rotary magnet 1870. At its contacts 1824, the relay R1820 opens a point in the circuit over which the magnet 1870 is energized during a trunk-hunting operation. At its contacts 1825, the relay R1820 opens a point in the path for connecting the test wiper 2053 to ground and in the circuit for energizing the test relay R1700. At its contacts 1826, the relay R1820 opens a point in the operating circuit for the all-trunks-busy relay R1710. At its contacts 1827, the relay R1820 opens a point in the operating circuit for the relay R1900.

The impulses of the second digit transmitted to the trunk circuit 26 from the toll office No. 1 are repeated by the signal relay R320 and the pulsing relay R660 over the loop circuit connecting the selector 32 with the trunk circuit 26. The line relay R1730, in following the impulses, functions to repeat the same to the vertical mag-

net 1817 and the transfer relay R1810, over a circuit which includes the contacts 1725, 1732, 1742 and 1812. The vertical magnet 1817, in following the impulses, functions to elevate the wipers 2051 to 2056, inclusive, to a position opposite the level of bank contacts corresponding to the numerical value of the received digit, so that at the end of the digit these wipers are left standing opposite the level of bank contacts in which are terminated the trunk circuit through which access is gained to the distant manual office No. 1. In this regard it will be noted that each time the line relay R1730 restores during the open-circuit period of an impulse, it opens its contacts 1731 to interrupt the operating circuit for the hold relay R1740. Due to its slow-to-release characteristic the last-mentioned relay remains operated during impulsion. Each time the line relay R1730 releases, it also opens its contacts 1733 to interrupt the prepared operating circuit for the rotary magnet 2041 of the minor switch 2040.

Incident to the vertical off-normal movement of the wipers 2051 to 2056, inclusive, the off-normal springs 1747 are closed to prepare the operating circuit for the release magnet 1748; the off-normal springs 1748 are closed to prepare the operating circuit for the rotary magnet 1870; and the off-normal springs 1801 are opened to deenergize the lower winding of the transfer relay R1810. This relay, due to its slow-to-release characteristic, remains in its operated position so long as current pulses are transmitted thereto under the control of the line relay R1730, i. e., throughout the first digit transmitted to the toll selector 32. At the end of this digit and during the inter-digit pause separating the same from the next succeeding digit, the line relay R1730 remains in its operated position for an interval of sufficient length to permit the transfer relay R1810 to release.

Upon restoring, the transfer relay R1810 opens its contacts 1811 to interrupt the operating circuit for the transfer relay R1820. At its contacts 1812, the relay R1810 opens the circuit for energizing its own upper winding in parallel with the vertical magnet 1817. At its contacts 1813, the relay R1810 further prepares the circuit for transmitting current pulses to the rotary magnet 1870 and the transfer relay R1830 in parallel under the control of the line relay R1730. At its contacts 1814, the relay R1810 prepares the automatic hunting circuit over which the rotary magnet 1870 is energized on a call through the selector 32 to a one digit trunk level. At its contacts 1815, the relay R1810 opens a point in the prepared path for impressing ground potential upon the test wiper 2053. At its contacts 1816, the relay R1810 reprepares the circuit for energizing the test relay R1700. Following the release of the relay R1810 the toll selector 32 is conditioned to respond to the impulses of the third digit as transmitted to the trunk circuit 26 from the distant toll office No. 1.

The second digit as dialed into the selector 32 through the selector 37 and the trunk circuit 26 from the distant toll office No. 1 is utilized to position the wipers 2051 to 2056, inclusive, on the contacts terminating the conductors of the first trunk circuit through which access may be gained to the manual office No. 1. In following the impulses of this digit, the line relay R1730 intermittently energizes the transfer relay R1830 over a circuit which includes the contacts 1725, 1732, 1742 and 1813. It also functions to re-

peat the impulses to the rotary magnet 1870 over a circuit which includes the contacts 1725, 1732, 1742, 1813 and 1823. The rotary magnet 1870, in following the impulses, functions to rotate the wipers 2051 to 2056, inclusive, at the rate of one step for each impulse, so that at the end of the digit these wipers are left standing in engagement with the contacts which terminate the access conductors of the first trunk circuit in the selected group. The transfer relay R1830, upon operating at the beginning of the digit, closes its contacts 1831 to complete an obvious circuit for energizing the relay R1860. At its contacts 1832, the relay R1830 closes an obvious multiple holding circuit for the transfer relay R1820. At its contacts 1833, the relay R1830 opens a point in the prepared circuit for energizing the test relay R1700. Due to its slow-to-release characteristic, the transfer relay R1830 remains operated throughout the digit and only restores shortly after the digit is ended.

The relay R1860, upon operating, locks to ground through the contacts 1861 and 1821. At its contacts 1862, the relay R1860 opens a point in the initially completed locking circuit for the transfer relay R1820. At its contacts 1863, the relay R1860 completes an obvious circuit for energizing the lower winding of the relay R1840. At its contacts 1864, the relay R1860 opens a point in the paths for impressing resistance battery potential upon the E. C. conductor C1706 of the trunk 32d. At its contacts 1865, the relay R1860 opens a point in the circuit for energizing the rotary magnet 1870 during an automatic trunk hunting operation. At its contacts 1866, the relay R1860 prepares the circuit for energizing the test relay R1700.

The relay R1840, upon operating, locks to ground through the contacts 1841 and 1725. At its contacts 1842, the relay R1840 further prepares the above-mentioned paths for impressing resistance battery potential upon the E. C. conductor C1706. At its contacts 1843, the relay R1840 opens a point in the paths for connecting the E. C. conductor C1706 to ground in the selector 32 or to the E. C. wiper 2055. At its contacts 1844, the relay R1840 opens a point in the circuit for energizing the line relay R1730 in accordance with the ground pulses transmitted over the 120 I. P. M. lead C2637.

The transfer relay R1830, upon releasing at the end of the digit, opens its contacts 1831 to interrupt the operating circuit for the relay R1860. At its contacts 1832, the relay R1830 deenergizes the transfer relay R1820. At its contacts 1833, the relay R1830 completes the previously mentioned test circuit over which the winding of the test relay R1700 may be energized. In this regard it is pointed out that if the first trunk circuit in the selected group is idle, the test conductor thereof is marked with negative battery potential. On the other hand, if this trunk circuit is busy the test conductor thereof is marked with ground potential. Assuming first that the first trunk of the group is busy, no circuit is provided for energizing the test relay R1700. On the contrary, this relay is short-circuited over a path which includes the contacts 1745, 1816, 1713, 1866 and 1833, and the test wiper 2053. Thus the test relay is prevented from operating.

The transfer relay R1820, upon restoring in response to the release of the transfer relay R1830, closes its contacts 1825 to shunt the contacts 1866 as included in the above-traced path for short-

circuiting the winding of the test relay R1700. At its contacts 1821, the relay R1820 deenergizes the relay R1860. At its contacts 1823, the relay R1820 opens the above-traced circuit for transmitting impulses to the rotary magnet 1870. At its contacts 1826, the relay R1820 prepares the operating circuit for the all-trunks-busy relay R1710. At its contacts 1827, the relay R1820 prepares the operating circuit for the relay R1900. At its contacts 1824, the relay R1820 prepares the circuit over which the rotary magnet 1870 is energized during an automatic trunk hunting operation.

The relay R1860, upon restoring, opens its contacts 1861 further to interrupt its own locking circuit. At its contacts 1862, the relay R1860 reprepares the locking circuit for the transfer relay R1820. At its contacts 1863, the relay R1860 opens the operating circuit for the relay R1840. At its contacts 1866, the relay R1860 opens the shunt across the contacts 1825. At its contacts 1864, the relay R1860 closes the prepared circuit for energizing the relay R1910 in series with the transfer relay R550 of the trunk circuit 26, this circuit extending from ground by way of the winding of R550, the contacts 445, C178, the wiper 36d, C1338, the contacts 1419 and 1441', the wiper 1654, C1708, the contacts 1842, 1864 and 1903, the winding of R1910, and the right normal post springs 1915 to battery.

30 The relay R1910 operates when energized in series with the transfer relay R550 over the above-traced circuit. The resistance of this circuit is sufficiently high, however, to prevent the relay R550 from operating. Upon operating, the relay R1910 closes its contacts 1913 to complete a multiple circuit for energizing the lower winding of the relay R1840. At its contacts 1912, the relay R1910 completes an obvious circuit for energizing the switching relay R1930. At its contacts 1911, the relay R1910 opens a point in the path for connecting the negative terminal of the exchange battery to the talking conductor C1703. At its contacts 1914, the relay R1910 opens a point in one of the circuits for energizing the ringing control relay R2000.

40 The switching relay R1930, upon operating, locks to the grounded conductor C1705 through its contacts 1936. At its contacts 1932 and 1935, the relay R1930 prepares a path for bridging the repeating coil windings 2021 and 2022 across the talking conductors C1703 and C1704. At its contacts 1933, the relay R1930 prepares a path for bridging the repeating coil windings 2023 and 2024 across the talking wipers C2051 and C2052. At its contacts 1937, the relay R1930 opens a point in one of the circuits for energizing the relay R1840. At its contacts 1938, the relay R1930 prepares the operating circuit for the rering relay R2010. At its contacts 1939, the relay R1930 opens a point in the path for connecting the E. C. conductor C1706 to the E. C. wiper 2055. At its contacts 1931', the relay R1930 prepares a path for impressing ground potential upon the E. C. conductor C1706. At its contacts 1932', the relay R1930 prepares a multiple path for impressing ground potential upon the E. C. conductor C1706. At its contacts 1933', the relay R1930 opens a point in the operating circuits for the relays R1900 and R1940. At its contacts 1934', the relay R1930 opens a point in the locking circuit for the relay R1940.

50 In releasing, the relay R1860 also closes its contacts 1865 to complete the above-mentioned circuit for energizing the rotary magnet 1870 dur-

ing an automatic trunk hunting operation. This circuit extends from ground by way of the contacts 1744, 1701 and 1726, the off-normal springs 1746, the contacts 1814, 1824, 1865 and 1871, and the winding of the magnet 1870 to battery. Due to the circuit interrupting action of the contacts 1871 included in this circuit, the magnet 1870 operates buzzer fashion to rotate the wipers 2051 to 2056, inclusive, across the remaining contacts of the selected contact level until an idle trunk circuit in the selected group of trunk circuits is found, or until all of the trunk circuits in the group have been tested and found to be busy. In this regard it is pointed out that the contacts engaged by the wipers 2053 and 2054 in the contact set terminating the last trunk circuit of the group, are strapped together. Accordingly, if the wipers 2051 to 2056, inclusive, are operated to engage the contacts terminating the access conductors of the last trunk circuit of the group, and this trunk circuit is busy, ground potential is impressed upon both of the wipers 2053 and 2054. When the wiper 2054 is connected to ground, a circuit including the contacts 1826, 1728 and 1714 is completed for energizing the all-trunks-busy relay R1710. This relay, in operating, locks to the grounded conductor C1705 through its preliminary make contacts 1715 and then opens its operating circuit at the contacts 1714. At its contacts 1716, the relay R1710 opens a point in the operating circuit for the relay R1900. At its contacts 1713, the relay R1710 opens a point in the path short-circuiting the test relay R1700. At its contacts 1711, the relay R1710 opens a point in the path for transmitting ground pulses from the 120 I. P. M. lead C2637 over the E. C. conductor C1706 of the trunk 32d. At its contacts 1712, the relay R1710 prepares a path for transmitting ground pulses from the 60 I. P. M. lead C2638 over the E. C. conductor C1706. In opening its contacts 1713, the relay R1710 also interrupts the only available test circuit over which the test relay R1700 may be energized when an idle trunk circuit is encountered during the continued rotary movement of the selector wipers 2051 to 2056, inclusive. Accordingly, during the continued rotary movement of the wipers 2051 to 2056, inclusive, this test relay is rendered inoperative to test the idle or busy condition of the trunk circuits corresponding to the remaining rotary positions of the wipers.

When the wipers 2051 to 2056, inclusive, are rotated to the eleventh rotary off-normal positions thereof, the cam springs 1951 are opened to interrupt the path over which the E. C. conductor C1706 may be connected to the E. C. wiper 2055; the cam springs 1952 are closed further to prepare the path for transmitting ground pulses from the 60 I. P. M. lead C2638 over the E. C. conductor C1706 and through the selector 37 to the supervisory relay R540 of the trunk circuit 26; the cam springs 2013 are opened to prevent the ring control relay R2000 from operating; and the cam springs 1802 are closed to complete an obvious circuit for energizing the lower winding of the transfer relay R1810 in series with the winding of the test relay R1700. When the above-traced circuit for energizing the test relay R1700 in series with the lower winding of the transfer relay R1810 is completed, both relays operate. The relay R1700, upon operating, opens its contacts 1701 to interrupt the circuit for energizing the rotary magnet 1870, whereby rotary movement of the wipers 2051 to 2056, inclusive,

is arrested. At its contacts 1702, the relay R1700 completes the prepared operating circuit for the switching relay R1720, this circuit extending from ground by way of the contacts 1744 and 1702, and the winding of R1720 to battery.

The transfer relay R1810, upon reoperating, recompletes the operating circuit for the transfer relay R1820; closes its contacts 1812 to again prepare the circuit for energizing its own upper winding in parallel with the vertical magnet 1817; opens its contacts 1813 to interrupt the circuit for transmitting current pulses to the transfer relay R1830 and the rotary magnet 1870; opens its contacts 1814 further to interrupt the circuit for energizing the rotary magnet 1870 during the trunk hunting operation; closes its contacts 1815 to reprepare the path for connecting the test wiper 2053 to ground; and opens its contacts 1816 to interrupt the rotary test circuit. The reoperation of the transfer relay R1820 is without effect.

The switching relay R1720, upon operating, locks to the grounded conductor C1705 through its contacts 1721', and closes its contacts 1727 to short-circuit the test relay R1700 and provide a holding circuit for the transfer relay R1810. At its contacts 1722', the relay R1720 prepares the operating circuit for the relay R1940. At its contacts 1729, the relay R1720 prepares the operating circuit for the rering relay R2010 and also prepares the path for connecting the E. C. wiper 2055 to the E. C. conductor C1706 of the trunk 32d. At its contacts 1728, the relay R1720 opens another point in the operating circuit for the all-trunks-busy relay R1710. At its contacts 1726, the relay R1720 opens another point in the circuit for energizing the rotary magnet 1870 during a trunk hunting operation. At its contacts 1725, the relay R1720 opens the locking circuit for the relay R1840 and interrupts the previously traced circuits for energizing the hold relay R1740, the upper winding of the transfer relay R1810, the vertical magnet 1817, the transfer relay R1830 and the rotary magnet 1870. At its contacts 1721 and 1723, the relay R1720 opens two points in the loop circuit connecting the trunk circuit 26 with the selector 32. When this loop circuit is opened, both the line relay R1730 and the loop seizure relay R650 are deenergized and restore. At its contacts 1722 and 1724, the relay R1720 connects the line terminals of the repeating coil windings 2021 and 2022 to the talking conductors C1703 and C1704, thereby to prepare a simplex circuit for energizing the simplex relay R680 of the trunk circuit 26 in series with the relay R1920 of the selector 32.

The relay R1700, upon restoring, opens its contacts 1702 to interrupt the operating circuit for the switching relay R1720, and recloses its contacts 1701 to reprepare the circuit for energizing the rotary magnet 1870 during a trunk hunting operation. The line relay R1730, upon restoring, opens its contacts 1731 further to interrupt the operating circuit for the hold relay R1740, and closes its contacts 1732 to reprepare the previously traced circuits for energizing the relays R1810 and R1830 and the two magnets 1817 and 1870. At its contacts 1733, the relay R1730 opens a point in the prepared operating circuit for the rotary magnet 2041.

The hold relay R1740, upon restoring, opens its contacts 1741 to disconnect the conductor C1705 from ground in the toll selector 32, and thus interrupt the established multiple holding circuits

for the operated relays R1720 and R1930. This trunk conductor is, however, connected to ground in the selector 31, whereby the two relays R1720 and R1930 are prevented from releasing. At its contacts 1743, the relay R1740 prepares the operating circuit for the release magnet 1748. At its contacts 1744, the relay R1740 opens a point in the common portion of the above-traced circuits for energizing the switching relay R1720 and the rotary magnet 1870. At its contacts 1745, the relay R1740 opens a point in the operating circuits for the test relay R1700 and the paths for short-circuiting the winding of this test relay.

When the loop seizure relay R650 is deenergized and releases, it causes the control equipment of the trunk circuit 26 to be shifted to its simplex pulse setting in the manner previously explained. From this explanation it will be recalled that the relays R430, R440, R670 and R680 are operated in the trunk circuit 26, after the control equipment of this trunk circuit is shifted from its loop pulsing setting to its simplex pulse setting. It will also be understood that the simplex relay R680 is energized in series with the relay R1920 of the selector 32 after the shift from one setting to the other is fully completed in the trunk circuit 26. Incident to the operation of the switching relay R440, the contacts 445 are opened to interrupt the previously traced circuit for energizing the relay R1910, and the contacts 446 are closed to prepare a circuit for energizing the supervisory relay R540 in accordance with the ground pulses being transmitted over the 60 I. P. M. lead C2638.

When the relay R1910 is deenergized in the selector 32, it closes its contacts 1911 to complete the other half of the simplex circuit over which the simplex relay R680 is energized in series with the relay R1920. At its contacts 1912, the relay R1910 interrupts the operating circuit for the relay R1930. At its contacts 1913, the relay R1910 deenergizes the relay R1840. At its contacts 1914, the relay R1910 prepares the operating circuit for the ringing control relay R2000. The relay R1920, upon operating, closes its contacts 1921 further to prepare the operating circuit for the ringing control relay R2000.

The relay R1840, upon restoring, opens its contacts 1841 further to interrupt its own locking circuit. At its contacts 1842, the relay R1840 opens another point in the circuit for energizing the relay R1910. At its contacts 1844, the relay R1840 prepares a circuit for energizing the line relay R1730 in accordance with the ground pulses transmitted over the 120 I. P. M. lead C2637. At its contacts 1845, the relay R1840 opens a point in the operating circuit for the relay R1900. At its contacts 1846, the relay R1840 prepares the operating circuit for the ringing control relay R1940. At its contacts 1843, the relay R1840 completes the above-mentioned circuit for energizing the supervisory relay R540 in accordance with the ground pulses transmitted over the 60 I. P. M. lead C2638, this circuit extending from the indicated pulsing lead by way of the contacts 1712, the cam springs 1952, the contacts 1843, C1706, the wiper 1654, the contacts 1441' and 1419, C1338, the wiper 36d, C778, the contacts 446, and the upper winding of R540 to battery. In following the impulses transmitted over this circuit the supervisory relay R540 alternately applies ground and negative battery potentials to the signal lead C325, whereby a flash busy signal is produced by the supervisory lamp associ-

ated with the connection in the toll office No. 1. The flashing of this lamp at the indicated rate of 60 flashes per minute serves to inform the operator handling the call in the toll office No. 1 that an all-trunks-busy condition has been encountered in the final switching stage of the toll train. The manner in which the connection may be released under the control of this operator is explained below.

- 10 To consider the manner in which an idle ring-down trunk circuit is seized through the outlet contacts of the toll selector 32, it may be assumed that the trunk circuit 28 is the first idle trunk in the selected group at the time the above-described trunk hunting operation of the selector 32 is initiated. Under these circumstances, the test relay R1700 is short-circuited during the trunk hunting operation until such time as the test wiper 2053 engages the test contact at which 15 the test conductor of the trunk 28f is terminated. Since this test conductor is marked with negative battery potential, the test relay R1700 is energized in a circuit including the test wiper 2053, the contacts 1833, 1825, 1713, 1818 and 1745. 20 When thus energized, the relay R1700 opens its contacts 1701 to deenergize the rotary magnet 1870 and thus arrest the rotary movement of the wipers 2051 to 2056, inclusive, with these wipers positioned to engage the contacts terminating 25 the conductors of the trunk 28f. At its contacts 1702, the relay R1700 completes the above-traced operating circuit for the switching relay R1720. The switching relay R1720, upon operating, deenergizes the line relay R1730, extends the loop 30 circuit to the repeating coil 2020, deenergizes the hold relay R1740, opens the automatic trunk hunting circuit, short-circuits the test relay R1700, interrupts the operating circuit for the all-trunks busy relay R1710, and locks to the 35 grounded lead C1705, all in a manner explained above. The release of the test relay R1700 is without effect. The release of the line and hold relays R1730 and R1740, respectively, is also without effect.
- 40 In operating, the relay R1720 also deenergizes the loop seizure relay R650 to cause the control equipment of the trunk circuit 26 to shift from its loop pulse setting to its simplex pulse setting, in the manner previously explained. Incident to 45 this operation, and more specifically when the control relay R440 operates, the relay R1910 is deenergized and restores. Also incident to this operation, the simplex relay R680 is energized in series with the relay R1920. The relay R1910, 50 upon restoring, closes its contacts 1911 to complete the other side of the simplex circuit over which the two relays R680 and R1920 are energized in series. At its contacts 1913, the relay R1910 deenergizes the relay R1840. At its contacts 1914, the relay R1910 prepares the operating circuit for the ringing control relay R2000. At its contacts 1912, the relay R1910 opens the operating circuit for the switching relay R1930 but the latter relay remains locked up through its 55 locking contacts 1936.
- The relay R1840, upon restoring, closes its contacts 1844 to prepare the previously mentioned circuit for energizing the line relay R1730 in accordance with the ground pulses transmitted over the 120 I. P. M. lead C2637. At its contacts 1842, the relay R1840 opens another point in the circuit for energizing the relay R1910. At its contacts 1845, the relay R1840 opens a point in the prepared operating circuit for the relay R1900. At its contacts 1846, the relay R1840

prepares the operating circuit for the ringing control relay R1940. At its contacts 1843, the relay R1840 completes a path through the cam springs 1951 and 2013, and the contacts 1931' and 2011 for impressing ground potential upon the connected E. C. conductors C1706, C1338 and C178, whereby the supervisory relay R540 is operated in the trunk circuit 28. This supervisory relay, upon operating, substitutes negative battery potential for ground potential upon the signal lead C325, whereby a supervisory signal is produced before the operator handling the call in the toll office No. 1, which indicates that the desired called trunk has been seized and the called office is being signaled thereover.

When energized in series with the simplex relay R680 of the trunk circuit 28, the relay R1920 closes its contacts 1921 to complete the operating circuit for the ringing control relay R2000, this circuit extending from ground by way of the cam springs 2013, the contacts 2002, the off-normal springs 2044 of the minor switch 2040, the contacts 1914 and 1921, and the winding of R2000 to battery. In operating, the relay R2000 first locks to ground through its preliminary make contacts 2005 and the contacts 1921. After completing this locking circuit, the relay R2000 opens its operating circuit at the contacts 2002. At its contacts 2006, the relay R2000 prepares a circuit for transmitting current impulses to the rotary magnet 2041 of the minor switch 2040. At its contacts 2004, the relay R2000 prepares a path for impressing ground potential upon the E. C. conductor C1706. At its contacts 2003, the relay R2000 completes a circuit including the cam springs 2013 and the contacts 1943 for energizing the ringing relay R2030. At its contacts 2001, the relay R2000 completes the above-mentioned circuit for energizing the line relay R1730 in accordance with the ground pulses transmitted over the 120 I. P. M. lead C2637, this circuit extending from the lead C2637 by way of the contacts 1711, the resistor 1947, the contacts 2001, 1942 and 1844, and the upper winding of R1730 to battery.

The ringing relay R2030, upon operating, closes its contacts 2036 to complete an obvious circuit for energizing the slow-acting hold relay R1740. At its contacts 2031 and 2034, the relay R2030 disconnects the talking wipers 2051 and 2052 from the line terminals of the repeating coil windings 2023 and 2024. At its contacts 2033', the relay R2030 bridges the terminating impedance 2027, 2028 across the line terminals of the repeating coil windings 2023 and 2024. At its contacts 2032 and 2035, the relay R2030 completes a circuit for transmitting ringing current to the trunk circuit 28. Thus it will be noted that, with these contacts closed, the negative talking wiper 2051 is connected to the ungrounded terminal of the ringing current generator over the conductor C4055, and the other talking wiper 2052 is connected to the grounded terminal of the ringing current generator. At its contacts 2033, the relay R2030 completes a path through the condenser 2037 for transmitting ringing current over the calling end of the connection, whereby the ringing signal may be audibly reproduced at the calling operator position in the toll office No. 1 if the operator handling the call remains on the connection until it is extended to the desired switchboard in the manual office No. 1.

The hold relay R1740, upon operating, closes its contacts 1744 to complete a multiple path for impressing ground potential upon the E. C. con-

ductor C1706, this path extending from ground by way of the contacts 1744, 1932', 2004 and 1931', the cam springs 1951, and the contacts 1843 to the conductor C1706. Thus a multiple circuit is provided for holding the supervisory relay R540 of the trunk circuit 28 operated. The remaining circuit switching operations performed by the hold relay R1740 are without effect.

The line relay R1730, in responding to the impulses transmitted thereto over the pulsing lead C2637, functions to repeat these impulses to the rotary magnet 2041 of the minor switch 2040. Thus each time this line relay operates, it closes its contacts 1733 to energize the magnet 2041 in a circuit which also includes the contacts 1944 and 2006. Each time the magnet 2041 is energized in this circuit it operates to advance the wiper 2045 one step. Incident to the off-normal movement of this wiper, the off-normal springs 2044 are opened further to interrupt the operating circuit for the ringing control relay R2000, and the off-normal springs 2043 are closed to prepare the operating circuit for the release magnet 2042. After the wiper 2045 has been rotated four steps away from its normal position to measure an elapsed time interval of approximately two seconds, it is moved to engage its associated fourth contact wherein the operating circuit for the ringing control relay R1940 is completed. This circuit extends from ground by way of the cam springs 2013, the contacts 2003, the wiper 2045 and its associated fourth contact, and the winding of R1940 to battery.

In operating, the ringing control relay R1940 closes its contacts 1941 to prepare an alternative circuit for energizing the relay R1840. At its contacts 1942, the relay R1940 interrupts the above-traced circuit for transmitting ground impulses to the line relay R1730, whereby the intermittent operation of this relay and the rotary magnet 2041 is arrested. At its contacts 1943, the relay R1940 deenergizes the ringing relay R2030. At its contacts 1944, the relay R1940 opens the above-traced circuit for energizing the rotary magnet 2041. At its contacts 1945, the relay R1940 opens a point in the available operating circuits for itself and the relay R1900. At its contacts 1946, the relay R1940 prepares a locking circuit for itself.

The ringing relay R2030, in releasing, opens its contacts 2032 and 2035 to disconnect the talking wipers 2051 and 2052 from the ringing current source and thus terminate the ring-down signal transmitted to the trunk circuit 28. At its contacts 2031 and 2034, the relay R2030 reconnects the talking wipers 2051 and 2052 to the line terminals of the repeating coil windings 2023 and 2024. At its contacts 2033', the relay R2030 interrupts the above-described ring-back tone signaling circuit. At its contacts 2033', the relay R2030 disconnects the terminating impedance 2027, 2028 from the line terminals of the repeating coil windings 2023 and 2024. At its contacts 2036, the relay R2030 deenergizes the hold relay R1740.

It is noted that when the ring-down signal is transmitted to the trunk circuit 28 over the talking leads of the trunk 28f is terminated, certain of the relays of this trunk circuit, which are energized during the ringing interval, are de-energized and restored. In releasing, these relays function momentarily to connect the E. C. conductor of the trunk 28f to ground, thereby momentarily to energize the ringing relay R2010 in a circuit which includes this conductor, the wiper 2055, and the contacts 1729 and 1938. During

the short interval when the rering relay R2010 is energized over this circuit, the contacts 2011 are opened to disconnect the E. C. conductor C1706 from ground through the cam springs 2013. In order to prevent this momentary and incidental operation of the rering relay R2010 from producing a flash of the supervisory lamp associated with the connection in the toll office No. 1, the hold relay R1740 is held operated during, and for a short time interval following, the ringing period. With this relay operated the previously traced path through the contacts 1744 is completed for maintaining ground potential upon the E. C. conductor C1706. The period during which the hold relay R1740 remains operated after the ringing interval is terminated, completely overlaps the short interval during whch the rering relay R2010 is operated. Accordingly, ground potential is maintained upon the E. C. conductor C1706 to prevent the momentary release of the supervisory relay R540 and the consequent flashing of the supervisory lamp associated with the connection in the toll office No. 1.

The ringing current transmitted through the ring-down trunk circuit 28 and over the trunk 7 effects the operation of an incoming call signal device associated with the trunk 7 at one or more positions of the switchboard 41 in the distant manual office No. 1.

If the operator handling the call in the toll office No. 1 fails to get a response from the called manual office No. 1 within a reasonable time interval after the answer or off-hook supervisory signal is produced by the signal lamp associated with the connection in the toll office, she may rering the called manual office by transmitting a 50-120 millisecond open-circuit pulse to the signal relay R320 over the trunk 5. During this rering pulse, the signal relay R320 is released so that the contacts 321 thereof are opened to deenergize the simplex relay R680 and the relay R1920 in the selector 32. The simplex slave relay R670 may open its contacts 672 to interrupt the operating circuit for the slow-acting hold relay R710 during the period of the rering pulse. The release periods of the two relays R670 and R710 in combination, however, exceed the duration of the rering pulse and, accordingly, the hold relay R710 is prevented from releasing. At the end of the rering pulse, the two sides of the trunk 5 are again connected to the negative terminal of the battery provided in the toll office No. 1, whereby the relays R320, R680 and R1920, and the relay R670 if released, are again energized.

The relay R1920, upon restoring at the beginning of the rering pulse transmitted thereto by the signal relay R320, opens its contacts 1921 to deenergize the ringing control relay R2000. The relay R2000, upon restoring, closes its contacts 2002 to energize the release magnet 2042 in a circuit which includes the cam springs 2013 and the off-normal springs 2043. The magnet 2042, upon operating, attracts its associated holding pawl, permitting the wiper 2045 to be restored to normal. Incident to the release of this wiper the off-normal springs 2043 are opened to deenergize the release magnet 2042 and the off-normal springs 2044 are closed to reprepare the operating circuit for the ringing control relay R2000. Following the release of the minor switch 2040 and the ringing control relay R2000, the ringing equipment of the selector 32 is reconditioned for another cycle of operation. In this regard it will be understood that when the relay R1920 reoperates, the operating circuit for the

ringing control relay R2000 is recompleted. From this point on the manner in which the ringing equipment of the selector functions to transmit ringing current to the trunk circuit 28 is exactly the same as explained above.

When the call is answered at one of the positions of the switchboard 41 in the manual office No. 1, the operator handling the call in the toll office No. 1 may converse with the answering operator in the manual office No. 1 and instruct the answering operator as to the name or telephone number of the desired party. Upon receiving these instructions the answer operator at the switchboard 41 may extend the call to the desired substation in the manner conventionally followed in manual office practice. After the connection is released at the called end thereof and the operator handling the call at the switchboard 41 receives disconnect supervision, she may repeat this supervision to the operator handling the call in the toll office No. 1 by ringing down the trunk circuit 28. More specifically, when ringing current is transmitted over the trunk 7 from the switchboard 41 the ringing relays of the trunk circuit 28 operate to connect the E. C. conductor of the trunk 28f to ground, thereby to complete the previously traced operating circuit for the rering relay R2010. The relay R2010, upon operating, opens its contacts 2011 to disconnect the E. C. conductor C1706 of the trunk 32d from ground and thus effect the deenergization of the supervisory relay R540. This supervisory relay, upon restoring, substitutes ground potential for negative battery potential upon the signal lead C325, whereby an on-hook supervisory signal is produced by the supervisory lamp associated with the connection in the toll office No. 1. At the end of the ring-off signal period, the ringing relays of the trunk circuit 28 restore to deenergize the rering relay R2010, whereby the E. C. conductor C1706 is again connected to ground to effect the reoperation of the supervisory relay R540. This relay, in reoperating, causes an off-hook supervisory signal to be produced by the supervisory lamp associated with the connection in the toll office No. 1. From the above explanation it will be understood that if the operator handling the call in the manual office No. 1 transmits successive splashes of ringing current over the trunk 7 and the relays of the trunk circuit 28 are arranged to follow the pulses of ringing current to effect the intermittent operation of the rering relay R2010, a flashing recall signal may be produced by the supervisory lamp associated with the connection in the toll office No. 1 to inform the operator handling the call in this office that she is being recalled.

The operator handling the call in the toll office No. 1, upon receiving the ring-off signal in the manner just explained, may effect the release of the switch train in the central office 10 by disconnecting the two sides of the trunk 5 from the negative terminal of the battery in the toll office No. 1 to effect the release of the signal relay R320. This relay, in restoring, initiates the release of the trunk circuit 26 in the exact manner previously explained. In releasing, the signal relay R320 also deenergizes the relay R1920 in the toll selector 32, whereby the ringing control relay R2000 and the minor switch 2040 are released in the manner previously explained. Incident to the release of the trunk circuit 26, the conductor C177 is disconnected from ground to effect the release of the operated finder 36 and the relays R1410 and R1630 in the selector 37. The relay

R1410, upon restoring, closes its contacts 1411' to energize the release magnet 1310, whereby the selector 37 is restored to normal in a manner which will be clearly apparent from the above explanation. In releasing, the relay R1410 also opens its contacts 1416 to disconnect the conductor C1705 from ground and thus interrupt the holding circuits for the relays R1720 and R1930 in the selector 32. The relay R1720, upon restoring, closes its contacts 1725 to complete the prepared operating circuit for the release magnet 1748, this circuit also including the contacts 1732 and 1743 and the off-normal springs 1747. When thus energized, the release magnet 1748 attracts its associated holding pawl, permitting the wipers 2051 to 2056, inclusive, to be restored to rotary and vertical normal in the usual manner. Incident to the release of these wipers, the off-normal springs 1747 are opened to deenergize the release magnet 1748; the off-normal springs 1801 are closed to reprepare the operating circuit for the transfer relay R1810; and the off-normal springs 1746 are opened further to interrupt the previously traced circuit for energizing the rotary magnet 1870 during an automatic trunk hunting operation. Following the deenergization of the release magnet 1748 and the release of the two relays R1720 and R1930, the selector 32 is fully restored to normal. In this regard it will be noted that so long as the selector 32 is idle the test conductor C1705 thereof is marked with negative battery potential through the off-normal springs 1801 and the lower winding of the transfer relay R1810.

The manner in which the operated switch train comprising the trunk circuit 26, the selector 37 and the selector 32 is released in the event the call is not answered at the switchboard 41 in the distant manual office No. 1, is exactly the same as explained above. In the event an all-busy condition of the selected trunks extending to the manual office No. 1 is encountered, the cam springs 2013, 1802, 1951 and 1952 and the relays R1720, R1810, R1820 and R1930 are operated in the selector 32 at the time the release of the switch train is initiated. In this case, the release of the selector 32 proceeds in the exact manner explained above when the test conductor C1705 is disconnected from ground in the preceding selector 37. In this regard it will be understood that the relay R1820 is deenergized concurrently with the two switching relays R1720 and R1930 when the test conductor C1705 is disconnected from ground. The transfer relay R1810 is deenergized and restores when the switching relay R1720 restores to open the locking circuit therefor at the contacts 1727. The enumerated cam springs of the selector switching mechanism are restored to normal incident to the release of the wipers 2051 to 2056, inclusive, when the magnet 1748 is energized.

Routing the call to the manual office No. 2

If the above-described call originating in the toll office No. 1 and extended through the trunk circuit 26 and the selector 37 to the selector 32 is to be routed to a subscriber served by the manual office No. 2, the second digit dialed into the switching equipment of the central office 10 from the toll office No. 1 is utilized to position the wipers 2051 to 2056, inclusive, opposite the level of bank contacts through which access is gained to the selectors having access to trunks interconnecting the central office 10 with the manual office No. 2. More specifically, when the sec-

ond digit is dialed into the toll selector 32, the wipers of this selector are positioned opposite the level of bank contacts in which the conductors of the trunk 34 incoming to the toll selector 34 are terminated. Immediately the wipers of the selector 32 are moved to this position the left normal post springs 1803 are moved out of engagement to deenergize the transfer relay R1820.

In releasing, the transfer relay R1820 opens its contacts 1821 to interrupt the prepared locking circuit for the relay R1860. At its contacts 1822, the relay R1820 opens a point in its own locking circuit. At its contacts 1823, the relay R1820 opens the previously traced circuit for transmitting directive impulses to the rotary magnet 1870 under the control of the line relay R1730. At its contacts 1824, the relay R1820 prepares the previously traced circuit for energizing the rotary magnet 1870 during an automatic trunk hunting operation. At its contacts 1825, the relay R1820 prepares the previously traced trunk test circuit through the winding of the test relay R1700. At its contacts 1826, the relay R1820 prepares the previously traced operating circuit for the all-trunks-busy relay R1710. At its contacts 1827, the relay R1820 prepares the operating circuit for the relay R1900.

Shortly after the single digit transmitted to the toll selector 32 is ended, the transfer relay R1810 restores and closes its contacts 1814 to complete the previously traced circuit for energizing the rotary magnet 1870 through its self-interrupting contacts 1871. Thus the automatic trunk hunting operation of the selector 32 in the level of contacts selected during the vertical movement of the wipers 2051 to 2056, inclusive, is initiated. In this regard it will be noted that the trunk test circuit through the winding of the test relay R1700 is completed at the contacts 1816 incident to the release of the transfer relay R1810. The automatic trunk hunting operation proceeds in the exact manner explained above until a trunk extending to an idle toll selector of the selected group is found, or until all of the trunks of the selected group have been tested and found to be occupied with calls.

Assuming first that all of the toll selectors of the selected group are busy at the time the call under consideration is extended to the toll selector 32, the wipers of this toll selector are rotated to the eleventh off-normal positions thereof wherein the cam springs 1802 are closed to energize the test relay R1700 in series with the lower winding of the transfer relay R1810; the cam springs 2013 are opened to interrupt the prepared operating circuit for the ringing control relay R1000; the cam springs 1951 are opened to interrupt the prepared path for connecting the E. C. conductor C1706 to ground in the selector 32; and the cam springs 1952 are closed to complete the previously traced path for transmitting ground pulses from the 120 I. P. M. lead C2637 over the E. C. conductor C1706 to the trunk circuit 26.

The test relay R1700, upon operating, opens its contacts 1701 to deenergize the rotary magnet 1870 and thus arrest the rotary movement of the wipers 2051 to 2056, inclusive. At its contacts 1702, the relay R1700 completes the operating circuit for the switching relay R1720. The relay R1720, upon operating, initiates the release of the relays R1730, R1700 and R1740 in the exact manner previously explained with

reference to the all-trunks-busy condition encountered in extending the call to the manual office No. 1. In operating, the switching relay R1720 also opens the loop circuit connecting the selector 32 with the trunk circuit 26, whereby the control equipment of this trunk circuit is shifted into its simplex pulse setting. In response to the last-mentioned operation, the E. C. conductor C1706 is connected through the contacts 446 of the switching relay R440 to the supervisory relay R430, whereby this supervisory relay is rendered operative to repeat the flash busy signal to the toll operator handling the call in the distant toll office No. 1. In this case, the supervisory lamp associated with the connection in the toll office No. 1 is flashed at the rate of 120 flashes per minute, thus informing the operator that a blocked switching stage has been encountered at a point preceding the last switching stage of the desired connection. Upon receiving this signal, the operator handling the call at the toll switchboard in the toll office No. 1 may effect the release of the switch train in the central office 10 in the exact manner explained above.

It may be assumed now that the toll selector 34 is seized through the outlet contacts of the selector 32 during the automatic trunk hunting of the latter selector. In this regard it will be understood that when the wipers 2051 to 2058, inclusive, are rotated to engage the contacts terminating the conductors of the trunk 34f, the test relay R1700 is energized over the trunk test circuit. This circuit as extended to the selector 34 may be traced as including the contacts 1745, the winding of R1700, the contacts 1816, 1713, 1825 and 1833, the wiper 2053, C2105, the off-normal springs 2201, and the lower winding of the transfer relay R2210 to battery. When thus energized, the test relay R1700 operates to deenergize the rotary magnet 1870 and to complete the operating circuit for the switching relay R1720 in the manner previously explained. In this case the relay R1720, upon closing its contacts 1722 and 1724, extends the loop circuit from the trunk circuit 26 to the toll selector 34. This circuit as extended to the toll selector 34 includes the contacts 1931 and 1934, the contacts 2031 and 2034, the wipers 2051 and 2052, the talking conductors C2103 and C2104 of the trunk 34f, the contacts 2121 and 2123, the windings of the relay R2130, C2105, the wiper 2053, and the contacts 1833, 1825, 1713, 1816 and 1727. The extension of this loop circuit to the toll selector 34 prevents the loop seizure relay R650 from releasing in the trunk circuit 26. In operating, the switching relay R1720 also locks to the grounded conductor C1705 and effects the release of the three relays R1730, R1740 and R1700 in the manner previously explained. Thus following the switch-through operation of the selector 32 only the switching relay R1720 is operated therein.

When energized in the loop circuit as extended to the selector 32, the line relay R2130 closes its contacts 2131 to complete a circuit through the contacts 2128 for energizing the slow-acting hold relay R2140. At its contacts 2132, the relay R2130 opens a point in the common portion of the available circuits for energizing the release magnet 2146, the transfer relays R2210 and R2230, the vertical magnet 2217, and the rotary magnet 2260.

The hold relay R2140, upon operating, closes its contacts 2141 to complete an obvious multiple

path for impressing ground potential upon the test conductor C2105. At its contacts 2142, the relay R2140 prepares a point in the common portion of the available circuits for energizing the two transfer relays R2210 and R2230, the vertical magnet 2217 and the rotary magnet 2260. At its contacts 2143, the relay R2140 opens a point in the operating circuit for the release magnet 2146. At its contacts 2144, the relay R2140 prepares a circuit for energizing the rotary magnet 2260 through its self-interrupting contacts 2261, prepares a path for connecting the test wiper 2344 to ground, and prepares the operating circuit for the switching relay R2120. At its contacts 2145, the relay R2140 prepares the operating circuit for the test relay R2100.

When its lower winding is energized, first in series with the test relay R1700 and later through the contacts 1727 and 2141 in multiple, the transfer relay R2210 operates. At its contacts 2211, the relay R2210 completes a circuit including the normal post springs 2218 and the grounded conductor C2105 for energizing the transfer relay R2220. At its contacts 2212, the relay R2210 opens a point in the circuit for energizing the rotary magnet 2260 through its self-interrupting contacts 2261. At its contacts 2213, the relay R2210 opens a point in the circuit for transmitting directive impulses to the transfer relay R2230 and the rotary magnet 2260 in parallel. At its contacts 2214, the relay R2210 prepares a circuit for energizing its own upper winding in parallel with the vertical magnet 2217. At its contacts 2215, the relay R2210 prepares a path for impressing ground potential upon the test wiper 2344. At its contacts 2216, the relay R2210 opens a point in the trunk test circuit through the winding of the test relay R2100.

The relay R2220, upon operating, locks to the grounded conductor C2105 through the contacts 2221 and 2251, and the normal post springs 2218. At its contacts 2222, the relay R2220 opens a point in the operating circuit for the all-trunks-busy relay R2110. At its contacts 2223, the relay R2220 opens another point in the circuit for energizing the rotary magnet 2260 through its self-interrupting contacts 2261. At its contacts 2224, the relay R2220 prepares the circuit for energizing the rotary magnet 2260 in parallel with the transfer relay R2230. At its contacts 2225, the relay R2220 prepares a locking circuit for the relay R2250. At its contacts 2226, the relay R2220 opens a point in the trunk test circuit. At its contacts 2228, the relay R2220 opens a point in the operating circuit for the relay R2320. At its contacts 2227, the relay R2220 interrupts certain of the paths over which control signals may be transmitted over the E. C. conductor C2106 of the trunk 34f. Following the operation of the transfer relay R2210 to perform the functions just described, the selector 34 is conditioned to respond to the impulses of the third digit transmitted to the central office 10 from the toll office No. 1.

The first digit transmitted to the toll selector 34 from the toll office No. 1 is utilized to position the wipers 2341 to 2346, inclusive, opposite the level of bank contacts through which access is gained to the trunk circuits terminating the trunks extending to the manual office No. 2. More specifically, the line relay R2130 follows the operation of the signal relay R320 during this digit and functions to repeat the impulses of the digit to the vertical magnet 2217 and the transfer relay R2210 in parallel. Thus each time the relay R2130 restores during the open-circuit period of an impulse in-

cluded in this digit, it closes its contacts 2132 to energize the parallel-connected windings of the vertical magnet 2217 and the transfer relay R2210 in a circuit which includes the contacts 2128, 2142 and 2214. In releasing, the relay R2130 also opens its contacts 2131 to interrupt the operating circuit for the hold relay R2140. The latter relay, due to its slow-to-release character, remains operated during impulsing.

Each time the vertical magnet 2217 is energized in the above-traced circuit, it functions to elevate the wipers 2341 to 2346, inclusive, one step, so that at the end of the digit these wipers are left standing opposite the level of bank contacts corresponding to the numerical value of the digit. Incident to the vertical off-normal movement of the enumerated wipers the off-normal springs 2147 are closed to prepare the operating circuit for the release magnet 2146; the off-normal springs 2202 are closed to prepare the mentioned circuit for energizing the rotary magnet 2260 through its self-interrupting contacts 2261; and the off-normal springs 2201 are opened to de-energize the lower winding of the transfer relay R2210. Since this relay is of the slow-to-release type and receives the current pulses transmitted by the line relay R2130, it remains operated throughout the digit and for a short interval after the digit is ended. When the wipers of the selector 34 are positioned opposite the contact levels in which trunk circuits of the ring-down type are terminated, the right normal post springs 2312 are closed to prepare the operating circuit for the relay R2310. In the present case, wherein the group of trunks extending to the manual office No. 2 is desired by the calling operator, two digits must be transmitted to the selector 34 for the purpose of selecting the first trunk of this group. Accordingly, the left normal post springs 2218 are not disengaged during the vertical movement of the selector wipers.

Shortly after the digit initially transmitted to the selector 34 is ended, and during the inter-digit pause between this digit and the succeeding digit, the transfer relay R2210 opens its contacts 2211 to interrupt the operating circuit for the transfer relay R2220. At its contacts 2212, the relay R2210 prepares the circuit for energizing the rotary magnet 2260 through its self-interrupting contacts 2261. At its contacts 2213, the relay R2210 prepares the circuit for transmitting directive impulses to the transfer relay R2230 and the rotary magnet 2260 in parallel. At its contacts 2214, the relay R2210 opens the circuit for energizing its own upper winding in parallel with the vertical magnet 2217. At its contacts 2215, the relay R2210 opens the prepared path for connecting the test wiper 2344 to ground in the selector 34. At its contacts 2216, the relay R2210 prepares the previously mentioned trunk test circuit through the winding of the test relay R2100. Following the release of the transfer relay R2210 to perform the functions just described, the selector 34 is conditioned to respond to the impulses of the second digit transmitted thereto.

The impulses of this digit are repeated by the line relay **R2130** to the transfer relay **R2230** and the rotary magnet **2260** in parallel. More specifically, this impulsing circuit extends from ground by way of the contacts **2128**, **2132** and **2142** to the contacts **2213** where it divides, one branch extending through the winding of the transfer relay **R2230** to battery and the other branch extending through the contacts **2224** and the wind-

ing of the rotary magnet 2260 to battery. When initially energized in this circuit, the transfer relay R2230 closes its contacts 2231 to complete an obvious multiple holding circuit for the transfer relay R2220. At its contacts 2232, the relay R2230 completes an obvious operating circuit for the relay R2250. At its contacts 2233, the relay R2230 opens the previously mentioned trunk test circuit. Due to its slow-to-release characteristic, the transfer relay R2230 remains operated throughout the second series of impulses transmitted to the toll selector 34.

The relay R2250, upon operating, locks to ground through the contacts 2253 and 2225. At its contacts 2251, the relay R2250 opens the initially completed locking circuit for the transfer relay R2220. At its contacts 2252, the relay R2250 opens a point in the circuit for energizing the rotary magnet 2260 through its self-interrupting contacts 2261. At its contacts 2254, the relay R2250 completes an obvious circuit for energizing the relay R2240. At its contacts 2255, the relay R2250 closes an obvious shunt across the contacts 2226 of the transfer relay R2220. At its contacts 2256, the relay R2250 opens a point in the operating circuit for the relay R2310 and interrupts the paths over which control signals may be transmitted over the E. C. conductor C2106 of the trunk 34f.

30 The relay R2240, upon operating, locks to ground through the contacts 2241 and 2128. At its contacts 2242, the relay R2240 prepares the operating circuit for the relay R2310 and prepares the previously mentioned paths for transmitting control signals over the E. C. conductor C2106. At its contacts 2243, the relay R2240 opens a point in the path for transmitting flash busy ground pulses over the E. C. conductor C2106. At its contacts 2244, the relay R2240
35 prepares the operating circuit for the relay R2320. At its contacts 2245, the relay R2240 opens a point in the path for connecting the E. C. conductor C2107 to the E. C. wiper 2346.
40

45 Each time a current pulse is transmitted to the L. C. wiper 2340, the rotary magnet 2260 by the line relay R2130 to this magnet operates to step the wipers 2341 to 2346, inclusive, one step in the rotary direction. Accordingly, these wipers are left standing in engagement with the contacts terminating the conductors of the trunk extending to the first trunk circuit in the selected group at the end of the digit. Shortly after the digit is ended, the transfer relay R2230 restores and opens its contacts 2231 to deenergize the transfer relay R2220. 50 At its contacts 2232, the relay R2230 opens the operating circuit for the relay R2250. At its contacts 2233, the relay R2230 reprepares the trunk test circuit.

tacts 2228, the relay R2220 further prepares the operating circuit for the relay R2320.

In the event the selected first trunk circuit of the selected group is idle, the test relay R2100 is operated to open the automatic trunk hunting circuit through the rotary magnet 2260 and to close the operating circuit for the switching relay R2120, before the relay R2250 releases. On the other hand, if the first selected trunk circuit of the selected group is busy, the test conductor thereof is marked with ground potential so that the test relay R2100 is shunted over a path which includes the wiper 2344 and the contacts 2233, 2255, 2113, 2216 and 2145. In the latter case, the relay R2250, upon restoring, closes its contacts 2252 to complete the prepared circuit for energizing the rotary magnet 2260 through its self-interrupting contacts 2261, this circuit extending from ground by way of the contacts 2144, 2101 and 2121, the vertical off-normal springs 2202, the contacts 2212, 2223, 2252 and 2261, and the winding of the magnet 2260 to battery. In releasing, the relay R2250 also closes its contacts 2251 to reprepare the locking circuit for the transfer relay R2220. At its contacts 2253, the relay R2250 opens a second point in its own locking circuit. At its contacts 2254, the relay R2250 opens the operating circuit for the relay R2240. At its contacts 2255, the relay R2250 opens the shunt across the engaged break contacts 2226 included in the trunk test circuit. At its contacts 2256, the relay R2250 completes the operating circuit for the relay R2310, this circuit extending from ground by way of the winding of R550, the contacts 445, C178, the wiper 36d, C1338, the contacts 1419 and 1441', the wiper 1654, C1706, the contacts 1843, the cam springs 1951, the contacts 1939 and 1729, the wiper 2055, C2106, the contacts 2242, 2227, 2256 and 2323, the normal post springs 2312 and the winding of R2310 to battery. Due to the relatively high resistance of the winding of the relay R2310, the series-connected transfer relay R550 does not operate when energized in this circuit.

The relay R2310, upon operating, closes its contacts 2311 to complete an obvious circuit for energizing the relay R2300. In operating, the latter relay closes its contacts 2303 to complete an obvious multiple circuit for energizing the relay R2240. At its contacts 2301, the relay R2310 opens a point in the path for connecting the talking conductor C2103 to the talking wiper 2341. At its contacts 2302, the relay R2300 prepares a path for impressing resistance battery potential upon the talking conductor C2103. At its contacts 2305, the relay R2300 opens a point in the path for connecting the E. C. conductor C2107 to the E. C. wiper 2346. At its contacts 2304, the relay R2300 prepares a circuit for energizing the ringing control relay R1940 as provided in the preceding toll selector 32.

When energized in the above-traced trunk hunting circuit, the rotary magnet 2260 operates buzzer fashion to drive the wipers 2341 to 2346, inclusive, across the contacts of the selected contact level until an idle trunk circuit in the selected group is found or until all of the trunk circuits have been tested and found to be occupied with calls. Assuming first that an all-trunks-busy condition exists in the trunk circuits of the selected group, the enumerated wipers are rotated until they engage the contacts terminating the conductors of the trunk extending to the last trunk circuit of the group. In this set of contacts, the two contacts respectively engaged

by the wipers 2343 and 2344 are conductively strapped. Accordingly if the trunk circuit terminated at this contact set is busy, such that the two contacts engaged by the wipers 2343 and 2344 are connected to ground in the last trunk circuit of the group, the all-trunks-busy relay R2110 is energized in a circuit which includes the wiper 2343 and the contacts 2222, 2126 and 2112. When thus energized, the relay R2110

10 first locks to the grounded conductor C2105 through its preliminary make contacts 2111 and then opens its operating circuit at the contacts 2112. At its contacts 2113, the relay R2110 interrupts the path short-circuiting the winding of the test relay R2100. At its contacts 2114, the relay R2110 prepares a path for transmitting ground impulses from the 60 I. P. M. lead C2638 over the E. C. conductor C2106. At its contacts 2115, the relay R2110 opens a point in the available path for transmitting ground pulses from the 120 I. P. M. lead C2637 over the E. C. conductor C2106. At its contacts 2116, the relay R2110 opens a point in the operating circuit for the relay R2320.

25 From the above explanation it will be noted that the operation of the all-trunks-busy relay R2110 does not result in the operation of the test relay R2100. Accordingly the operating circuit for the rotary magnet 2260 is not opened and this magnet continues to drive the wipers 2341 to 2346, inclusive, across the contacts of the selected level. In this regard it will be noted that since the contacts 2113 are opened, the test relay R2100 is rendered ineffective to test the idle or busy condition of those trunks which may be terminated in the selected level of bank contacts at points following the trunks of the selected group. When the enumerated selector wipers are rotated to the eleventh off-normal positions thereof, the cam springs 2117 are closed further to prepare the path for transmitting ground pulses from the 60 I. P. M. lead C2638 over the E. C. conductor C2106; and the cam springs 2203 are closed to complete a circuit for energizing the test relay R2100 in series with the lower winding of the transfer relay R2210, this circuit extending from ground by way of the contacts 2145, the winding of R2100, the cam springs 2203, and the lower winding of R2210 to battery.

40 When thus energized, the test relay R2100 immediately opens its contacts 2101 to interrupt the circuit for energizing the rotary magnet 2260. Thus the rotary movement of the wipers 2341 to 2346, inclusive, is arrested with these wipers standing in their eleventh rotary off-normal positions. At its contacts 2102, the relay R2100 completes a circuit through the contacts 2144 for energizing the switching relay R2120.

45 The relay R2120, upon operating, opens its contacts 2121 and 2123 to deenergize the series-connected windings of the line relay R2130 and the loop seizure relay R650 in the trunk circuit 26. At its contacts 2122 and 2124, the relay R2120 connects the talking conductors C2103 and C2104 of the trunk 34f to resistance battery and the talking wiper 2342, respectively. At its contacts 2125, the relay R2120 locks to the grounded test conductor C2105. At its contacts 2126, the relay R2120 opens another point in the operating circuit for the all-trunks-busy relay R2110. At its contacts 2127, the relay R2120 opens another point in the circuit for energizing the rotary magnet 2260 through its self-interrupting contacts 2261. At its contacts 2128, the relay R2120 deenergizes the relays R2240 and R2140 and

opens a point in the common portion of the previously traced circuits for energizing the transfer relays R2210 and R2230, the vertical magnet 2217 and the rotary magnet 2260. At its contacts 2129, the relay R2120 completes an obvious holding circuit for the relay R2210 and in so doing short-circuits the relay R2100. At its contacts 2121, the relay R2120 prepares a path for connecting the E. C. conductor C2106 to the E. C. wiper 2345. At its contacts 2122', the relay R2120 completes the prepared operating circuit for the ringing control relay R1940, this circuit extending from ground by way of the contacts 2304 and 2122', C2107, the wiper 2056, the contacts 1945, 1933', 1904, 1846 and 1722', and the winding of R1940 to battery.

When its lower winding is energized, first in series with the test relay R2100 and later through the contacts 2129 of the switching relay R2120, the transfer relay R2210 closes its contacts 2211 to recomplete the operating circuit for the transfer relay R2220. At its contacts 2212, the relay R2210 opens another point in the circuit for energizing the rotary magnet 2260 through its self-interrupting contacts 2261. The remaining circuit switching operations performed incident to the reoperation of the transfer relay R2210 are without effect. The relay R2220, upon reoperating, locks to the grounded conductor C2105, opens another point in the operating circuit for the relay R2110, and opens another point in the circuit for energizing the rotary magnet 2260 through its self-interrupting contacts 2261. At its contacts 2226, the relay R2220 opens another point in the previously traced trunk test circuit. At its contacts 2227, the relay R2220 opens a point in the operating circuit for the relay R2310. At its contacts 2228, the relay R2220 opens a point in the operating circuit for the relay R2320.

The line relay R2130, upon restoring, opens its contacts 2131 further to interrupt the operating circuit for the hold relay R2140. At its contacts 2132, the relay R2130 prepares the operating circuit for the release magnet 2146. The hold relay R2140, upon restoring, opens its contacts 2141 to disconnect the test conductor C2105 from ground in the selector 34 and thus render this selector releasable under the control of the preceding selector 32. At its contacts 2143, the relay R2140 further prepares the operating circuit for the release magnet 2146. At its contacts 2144, the relay R2140 opens a point in the operating circuit for the switching relay R2120. At its contacts 2145, the relay R2140 opens a point in the trunk test circuit over which the test relay R2100 is controlled and interrupts the path short-circuiting the winding of the test relay. The test relay R2100, upon restoring, opens its contacts 2102 to interrupt the operating circuit for the switching relay R2120, and recloses its contacts 2101 to reprepare the circuit for energizing the rotary magnet 2260 through its self-interrupting contacts 2261.

As indicated above, the relay R2310 is deenergized in response to the reoperation of the transfer relay R2220. This circuit is also opened in the selector 32 incident to the operation of the ringing control relay R1940 in the manner explained above. When thus deenergized the relay R2310 opens its contacts 2311 to deenergize the relay R2300. The relay R2300, upon restoring, opens its contacts 2303 to deenergize the relay R2240. At its contacts 2304, the relay R2300 disconnects the E. C. lead C2107 from ground,

thereby to open a point in the common portion of the operating circuits for the relays R1940 and R1900 of the preceding selector 32. At its contacts 2305, the relay R2300 reprepares the path 5 for connecting the E. C. conductor C2107 to the E. C. wiper 2348.

The relay R2240, upon restoring, opens its contacts 2241 further to interrupt its own locking circuit. At its contacts 2242, the relay R2240 10 opens another point in the above-traced operating circuit for the relay R2210. At its contacts 2243, the relay R2240 completes the prepared path through the cam springs 2117 and the contacts 2114 for transmitting ground pulses from the 15 I. P. M. lead C2638 over the E. C. conductor C2106. Following the release of the relays R2130, R2140, R2310, R2300, R2240 and R2100, no further relay operations occur in the selector 34 until the connection is released under the control of 20 the operator handling the call in the distant toll office No. 1.

When the ringing control relay R1940 is energized in the selector 32 in the manner explained above, it locks to ground through its preliminary 25 make contacts 1946 and the contacts 1934'. At its contacts 1941, the relay R1940 completes a circuit through the contacts 1937 for energizing the relay R1840. At its contacts 1942, the relay R1940 opens a point in the previously traced circuit 30 for transmitting current impulses to the line relay R1730 from the 120 I. P. M. lead C2637. At its contacts 1943, the relay R1940 opens a point in the operating circuit for the ringing relay R2030. At its contacts 1944, the relay R1940 35 opens a point in the operating circuit for the rotary magnet 2041. At its contacts 1945, the relay R1940 opens a point in its own operating circuit.

The relay R1840, upon operating, closes its 40 contacts 1842 to complete the previously traced circuit for energizing the high resistance relay R1910 in series with the transfer relay R550 of the trunk circuit 26. After completing this circuit the relay R1840 opens its contacts 1843 to 45 interrupt the circuit for energizing the transfer relay R550 in series with the relay R2310, causing the latter relay to restore. At its contacts 1844, the relay R1840 opens another point in the circuit for transmitting current impulses to the line relay R1730 from the 120 I. P. M. lead C2637. At its contacts 1846, the relay R1840 opens another 50 point in the operating circuit for the ringing control relay R1940. At its contacts 1845, the relay R1840 prepares the operating circuit for the relay R1900.

The relay R1910, upon operating, closes its contacts 1912 to energize the switching relay R1930. At its contacts 1913, the relay R1910 55 closes a multiple circuit for energizing the relay R1840. At its contacts 1914, the relay R1910 opens a point in the operating circuit for the ringing control relay R2000. The switching relay R1930, in operating, opens its contacts 1931 and 1934, and closes its contacts 1932, 1933 and 1935, thereby to include the repeating coil 2020 in the connection between the trunk circuit 26 and the selector 34. At its contacts 1936, the relay R1930 locks to the grounded test conductor C1705. At its contacts 1937, the relay R1930 opens the 60 above-traced operating circuit for the relay R1840. At its contacts 1938, the relay R1930 prepares the operating circuit for the ringing relay R2010. At its contacts 1931', the relay R1930 prepares a path 65 for impressing ground potential upon the E. C. 70

conductor C1706. At its contacts 1933', the relay R1930 opens another point in the operating circuits for the relays R1940 and R1900. At its contacts 1934', the relay R1930 opens the locking circuit for the ringing control relay R1940.

The relay R1940, upon restoring, opens its contacts 1941 further to interrupt the above-traced operating circuit for the relay R1840. At its contacts 1942, the relay R1940 reprepares the circuit for transmitting impulses to the line relay R1730 from the 120 I. P. M. lead C2637. At its contacts 1943, the relay R1940 reprepares the operating circuit for the ringing relay R2030. At its contacts 1944, the relay R1940 reprepares the operating circuit for the rotary magnet 2041. At its contacts 1945, the relay R1940 reprepares the operating circuits for itself and the relay R1900. At its contacts 1946, the relay R1940 opens another point in its own locking circuit.

When the loop circuit connecting the trunk circuit 26 with the selector 34 is interrupted in the manner explained above, the loop seizure relay R650 is deenergized and restores. This relay, in releasing, causes the control equipment of the trunk circuit 26 to shift to its simplex pulse setting in the exact manner previously explained. Incident to this operation, the simplex relay R680 is energized in series with the relay R1920 of the selector 32, and negative battery potential, derived from the upper winding of the supervisory relay R540, is substituted for ground potential upon the connected E. C. conductors C178, C1338 and C1706, thereby to cause the deenergization and release of the relay R1910. The relay R1920, upon operating, closes its contacts 1921 to prepare the operating circuit for the ringing control relay R2000.

The relay R1910, upon restoring, closes its contacts 1911 to complete the parallel branch of the simplex circuit over which the relay R1920 is energized in series with the simplex relay R680. At its contacts 1912, the relay R1910 opens the operating circuit for the switching relay R1930. At its contacts 1913, the relay R1910 deenergizes the relay R1840. At its contacts 1914, the relay R1910 completes the prepared operating circuit for the ringing control relay R2000.

The relay R1840, upon restoring, opens its contacts 1842 further to interrupt the operating circuit for the relay R1910. At its contacts 1843, the relay R1840 connects the E. C. conductor C1706 to ground through the cam springs 1951, the contacts 1931' and 2011, and the cam springs 2013. A circuit is thus provided for energizing the supervisory relay R540 in the trunk circuit 26. This supervisory relay, upon operating, substitutes negative battery potential for ground potential upon the signal lead C325, whereby an off-hook supervisory signal is produced by the supervisory lamp associated with the connection in the distant toll office No. 1. In releasing, the relay R1840 also closes its contacts 1844 to prepare the previously traced circuit for transmitting current pulses from the 120 I. P. M. lead C2637 through the upper winding of the line relay R1730.

The ringing control relay R2000, upon operating, causes the talking wipers 2051 and 2052 to be connected to opposite terminals of the ringing current generator through the operated make contacts of the ringing relay R2030 for a two second ringing interval in the exact manner previously explained. In the present case, wherein the talking wipers 2341 and 2342 of the selector 34 are open-circuited, this ringing operation is

without effect. During the ringing interval, the slow-acting hold relay R1740 is energized through the make contacts 2036 of the ringing relay R2030 to maintain ground potential upon the

- 5 E. C. lead C1706 over a path which includes the contacts 1744, 1932', 2004 and 1931', the cam springs 1951 and the contacts 1843. Accordingly, the supervisory relay R540 is held operated during this interval.
- 10 At the end of the ringing interval, the relay R1940 reoperates to deenergize the ringing relay R2030 and to arrest the operation of the line relay R1730 and the minor switch 2040, all in the manner described above. Incident to the release of the relay R2030 the hold relay R1740 is deenergized and restores to interrupt the path through its contacts 1744 for holding ground potential upon the E. C. conductor C1706. In this regard it is noted that with the switching relay R1930 operated in the selector 32, the ground pulses as transmitted over the E. C. conductor C2106 from the 60 I. P. M. lead C2638 are utilized to effect the intermittent operation of the rering relay R2010, this relay being energized in a circuit which includes the grounded E. C. conductor C2106, the wiper 2055, and the contacts 1729 and 1938. This relay, in following the ground pulses, alternately opens and closes its contacts 2011, thereby intermittently to interrupt the path over which the E. C. conductor C1706 is connected to ground in the selector 32.

- From the above explanation, it will be understood that when the hold relay R1740 releases at the end of the ringing period, the rering relay R2010 in following the ground pulses transmitted thereto from the 60 I. P. M. lead C2638, is rendered effective to repeat these impulses to the supervisory relay R540. The supervisory relay R540, in turn, repeats the impulses over the signal lead C325, whereby a flash busy signal is produced by the supervisory lamp associated with the connection in the toll office No. 1. The rate at which this lamp is flashed, i. e., 60 flashes per minute, serves to inform the operator handling the call that the connection has proceeded to the last switching stage in the central office 10 where an all-trunks-busy condition has been encountered. Upon receiving this signal the operator may release the connection in the manner explained below.

- Assuming now that the trunk 29^f extending to the trunk circuit 29 is idle at the time the trunk hunting operation of the selector 34 is initiated in the manner explained above, this trunk and the associated trunk circuit 29 are seized through the outlet contacts of the selector. More specifically, when the wipers 2341 to 2346, inclusive, are rotated to engage the contacts terminating the conductors of the trunk 29^f, the above-mentioned 55 test circuit through the winding of the test relay R2100 is completed. This circuit extends from ground by way of the contacts 2145, the winding of R2100, the contacts 2216, 2113, 2226 and 2233, and the wiper 2344 to the negative terminal of the exchange battery as connected to the test conductor of the trunk 29^f in the trunk circuit 29. When energized in this circuit, the relay R2100 opens its contacts 2101 to interrupt the established circuit for energizing the rotary magnet 2260, whereby rotary movement of the wipers 2341 to 2346, inclusive, is arrested. At its contacts 2102, the relay R2100 completes the above-traced operating circuit for the switching relay R2120.

- 75 The switching relay R2120, upon operating,

locks to the grounded conductor C2105, deenergizes the relays R2130 and R2140, short-circuits the test relay R2100, deenergizes the loop seizure relay R650, and closes the operating circuit for the ringing control relay R1940 in the exact manner explained above. In this case, the relay R2120, upon operating, does not close a circuit for energizing the transfer relay R2210. Accordingly, the two relays R2210 and R2220 are not reoperated incident to the extension of the connection to the trunk circuit 29. In closing its contacts 2128, the relay R2120 does, however, complete a path through the contacts 2216, 2113, 2226 and 2233, and the wiper 2344 for connecting the test conductor of the trunk 29f to ground, thereby to mark this trunk and the associated trunk circuit 29 as busy in the bank contacts of the other selectors to which it is accessible. In operating, the switching relay R2120 also opens its contacts 2127 to interrupt the circuit for energizing the rotary magnet 2260 through its self-interrupting contacts 2261, thereby to prevent this magnet from again being energized in response to the release of the test relay R2100. The release of the three relays R2100, R2130 and R2140 is without effect.

When the previously traced operating circuit for the ringing control relay R1940 is completed through the contacts 2122' in response to operation of the switching relay R2120, the relay R1940 effects the operation of the relays R1840, R1910 and R1930 in the manner explained above. The relay R1930, upon operating, inserts the repeating coil 2020 in the connection between the trunk circuit 26 and the trunk circuit 29 and otherwise prepares the selector 32 for the transmission of ringing current to the seized trunk circuit 29, all in a manner which will be clearly apparent from the preceding explanation. From this explanation, it will also be recalled that when the loop circuit connecting the selector 34 with the trunk circuit 26 is opened, the control equipment of this trunk circuit is shifted to its simplex pulse setting. Incident to this shift in the setting of the control equipment in the trunk circuit 26, the simplex relay R680 is energized in series with the relay R1920, and negative battery potential is substituted for ground potential upon the connected E. C. conductors C1706, C1338 and C778 in the trunk circuit 26. Thus the relays R1920 and R1910 are respectively energized and deenergized in the selector 32 incident to the operation of the trunk circuit 26 to its simplex pulse setting.

When the two relays R1840 and R1930 operate in the manner just explained, the previously traced circuit for energizing the relay R2310 over the E. C. control path is opened at the contacts 1843 and 1939. In releasing, the relay R2310 opens its contacts 2311 to deenergize the relay R2300. The relay R2300, upon restoring, opens its contacts 2302 to disconnect the negative talking conductor C2103 from the negative terminal of the exchange battery, and closes its contacts 2301 to connect this talking conductor to the talking wiper 2341. At its contacts 2303, the relay R2300 deenergizes the relay R2240. At its contacts 2304, the relay R2300 disconnects the E. C. conductor C2107 from ground to open a point in the operating circuits for the relays R1900 and R1940. At its contacts 2305, the relay R2300 prepares a path for connecting the E. C. conductor C2107 to the E. C. wiper 2346.

The relay R2240, upon restoring, opens its contacts 2241 further to interrupt its own locking circuit. At its contacts 2243, the relay R2240 con-

ncts the E. C. conductor C2108 to the E. C. wiper 2345. At its contacts 2242, the relay R2240 opens another point in the operating circuit for the relay R2310. At its contacts 2244, the relay R2240 opens a point in the operating circuit for the relay R2320. At its contacts 2245, the relay R2240 completes the path for connecting the E. C. conductor C2107 to the E. C. wiper 2346.

When the relay R1920 operates and the relay 10 R1910 releases in the selector 32 in the manner explained above, the operating circuit for the ringing control relay R2000 is completed through the contacts 1914 and 1921. The relay R1910, in releasing, also opens its contacts 1913 to deenergize the relay R1840. The latter relay, upon 15 restoring opens its contacts 1842 further to interrupt the operating circuit for the relay R1910 and, at its contacts 1843, terminates the E. C. control path at ground through the cam springs 1951, the contacts 1931' and 2011, and the cam springs 2013. At its contacts 1844, the relay R1840 prepares the previously traced circuit for transmitting ground pulses to the line relay R1730 from the 120 I. P. M. lead C2637. At its 20 contacts 1845 and 1846, the relay R1840 opens a point in the operating circuit for the relay R1900, and reprepares one of the above-traced operating circuits for the ringing control relay R1940. When the E. C. control path extending 25 from the trunk 26 to the selector 32 is terminated at ground in this selector, the supervisory relay R540 operates to transmit an off-hook supervisory signal to the distant toll office No. 1 in the exact manner previously explained.

The relay R2000, upon operating, causes the 30 ringing equipment of the selector 32 to proceed through an operating cycle in the manner pointed out above. In this regard it will be recalled that when the wiper 2045 is operated to its fourth off-normal position to end the ringing period, the relay R1940 is operated to effect the deenergization of the relays R2030, R1730 and R1740. Thus the ringing operation is terminated. During the ringing interval, the negative 35 talking conductor of the trunk 29f is connected to the ungrounded terminal of the ringing current generator over a path which includes the wiper 2341, the contacts 2301 and 2122, C2103, the wiper 2051, the contacts 2032, and the ringing current conductor C4055. The other talking conductor of the trunk 29f is connected to the grounded terminal of the ringing current generator over a path which includes the wiper 2342, the contacts 2124, C2104, the wiper 2052, 40 and the contacts 2035. Thus ringing current is transmitted through the trunk circuit 29 and over the trunk 8 to energize the incoming call signal device associated with this trunk at the switchboard 42 in the distant manual office No. 2. 45 When the call is answered at the switchboard 42 in the manual office No. 2, the desired talking circuit is completed between the calling position of the operator switchboard in the toll office No. 1, and the answering position of the switchboard 42 in the manual office No. 2. Accordingly, the calling operator may instruct the answering operator as to the name or directory number of the desired subscriber, and the answering operator may extend the connection to the desired substation in the manner conventionally followed in manual office practice. If at any time before or after the talking circuit is completed between the switchboard in the toll office No. 1 and the switchboard 42 in the manual office No. 2, the calling operator desires to resig- 50 55 60 65 70 75

nal the called operator, she may, by a key operation or otherwise, disconnect the two sides of the trunk 5 from the negative terminal of the battery in the toll office No. 1 for a 50-120 millisecond interval. During this interval the relay R320 releases and opens its contacts 321 to deenergize the relay R1920 in the toll selector 32. The relay R1920, in restoring at the beginning of the 50-120 millisecond interval and in reoperating at the end of this interval, causes the ringing equipment of the toll selector 32 to operate through another cycle in the exact manner previously explained with reference to the extension of a connection to the manual office No. 1. It will be noted that this rering operation may be repeated as many times as desired under the control of the calling operator in the toll office No. 1.

If the answering operator in the manual office No. 2 desires to resignal the calling operator in the toll office No. 1, the ringing key at the answering position of the switchboard 42 is operated to project ringing current over the conductors of the trunk 8 for the purpose of energizing the ringing relays in the trunk circuit 29. During the ringing interval, the relay or relays of the trunk circuit 29 which respond to the ringing current operate to connect the E. C. conductor of the trunk 29f to ground, thereby to provide a circuit for energizing the rering relay R2010 of the selector 32. This circuit extends from the grounded E. C. wiper 2345 by way of the contacts 2121' and 2243, C2106, the wiper 2055, the contacts 1729 and 1938, and the winding of R2010 to battery. Each time the rering relay R2010 is energized in this circuit it opens its contacts 2011 to interrupt the ground termination of the E. C. control path which extends to the trunk circuit 26, thereby to deenergize the supervisory relay R540. This relay, upon restoring, transmits an on-hook supervisory signal over the trunk 5 to the toll office No. 1. When the conductors of the trunk 8 are disconnected from the ringing current generator in the manual office No. 2 the ringing relays of the trunk circuit 29 function to disconnect the E. C. conductor of the trunk 29f from ground and thus effect the sequential release of the rering relay R2010 and reoperation of the supervisory relay D540. The latter relay, in reoperating, transmits an off-hook supervisory signal to the operator handling the call in the distant toll office No. 1.

When the subscriber served by the manual office No. 2 disconnects, the operator handling the call in this office may transmit a short ring-off signal to the trunk circuit 29, whereby a short on-hook supervisory signal is transmitted to the operator handling the call in the toll office No. 1. After transmitting this signal, the operator handling the call in the manual office No. 2 may take down the connection as extended through the switchboard 42. The release of the operated switch train in the central office 10 is entirely under the control of the originating operator in the toll office No. 1. More specifically, when this operator releases the connection as set up through the toll switchboard in this toll office, the trunk circuit 26, the finder 36, the selector 31, and the selector 32 are released in the exact manner explained above with reference to the call routed to the manual office No. 1. Incident to the release of the selector 32 the test wiper 2053 and the test conductor C2105 are disconnected from ground at the contacts 1721. When ground potential is removed from the test con-

ductor C2105, the switching relay R2120 is deenergized and restores. This relay, in releasing, closes its contacts 2128 to energize the release magnet 2146 through the contacts 2132 and 2143, and the off-normal springs 2147. The release magnet 2146, in operating, attracts its associated holding pawl, permitting the wipers 2341 to 2346, inclusive, to be restored to their respective normal positions. Incident to the release of these wipers, the off-normal springs 2201 are closed to reprepare the operating circuit for the transfer relay R2210; the off-normal springs 2202 are opened further to interrupt the circuit for energizing the rotary magnet 2260 through its self-interrupting contacts 2261; the normal post springs 2312 are opened further to interrupt the operating circuit for the relay R2310; and the off-normal springs 2147 are opened to deenergize the release magnet 2146. Following the release of this magnet, the selector 34 is fully restored to normal. In this regard it is pointed out that the switching relay R2120, upon releasing, opens its contacts 2129 to disconnect the test conductor of the trunk 29f from ground, thereby to unguard the trunk circuit 29 and render this circuit available for use in handling other calls.

In the event the connection is released under the normal of the operator handling the call in the toll office No. 1 after an all-trunks-busy condition is encountered in the outlet contacts of the selector 34, the relays R2110, R2120, R2210 and R2220 are operated in this selector when the calling operator disconnects. In this case, the three relays R2110, R2120 and R2220 are deenergized and restore when the test conductor C2105 is disconnected from ground in the preceding selector 32. The relay R2120, upon restoring, opens its contacts 2129 to deenergize the transfer relay R2210. In restoring, the relay R2120 also closes the above-traced operating circuit for the release magnet 2146, whereby the wipers 2341 to 2346, inclusive, are restored to normal. Incident to the release of these wipers the vertical off-normal springs 2147 are opened to deenergize the release magnet 2146. Also incident to the release of the enumerated wipers the normal post springs 2312 are disengaged, the cam springs 2203 are opened, and the cam springs 2117 are opened.

Routing the call to the automatic exchange 3

The trunk circuits associated with the trunks extending to the automatic exchange 3 are terminated in the one digit contact levels of the contact bank of the toll selector 34. It will be understood, therefore, that if the above-described call originating in the toll office No. 1 and routed through the trunk circuit 26, the link 35 and the selector 32 to the selector 34 is to be extended to the automatic exchange 3, a single digit is transmitted to the toll selector 34 under the control of the calling device or register sender associated with the connection in the toll office No. 1. The impulses of this digit are utilized to position the wipers opposite the level of bank contacts in which the conductors of the trunk 4f are terminated. In this case, the right normal post springs 2312 are not operated into engagement during the vertical movement of the selector wipers. The left normal post springs 2218 are, however, disengaged to deenergize the transfer relay R2220 immediately the wipers 2341 to 2346, inclusive, are positioned opposite the level of contacts through the trunk circuit 4 may

be seized. In releasing, the relay R2220 opens its contacts 2221 further to interrupt its own locking circuit. At its contacts 2222, the relay R2220 prepares the previously traced circuit for energizing the all-trunks-busy relay R2110. At its contacts 2223, the relay R2220 prepares the circuit for energizing the rotary magnet 2260 through its self-interrupting contacts 2261. At its contacts 2224, the relay R2220 opens the circuit for directly controlling the rotary magnet 2260. At its contacts 2225, the relay R2220 opens a point in the locking circuit for the relay R2250. At its contacts 2226, the relay R2220 prepares the previously traced trunk test circuit. At its contacts 2227, the relay R2220 prepares the operating circuit for the relay R2310. At its contacts 2228, the relay R2220 prepares the operating circuit for the relay R2320.

Shortly after the transfer relay R2220 restores, and more specifically when the transfer relay R2210 releases at the end of the digit, the above-traced circuit for energizing the rotary magnet 2260 through its self-interrupting contacts 2261 is completed at the contacts 2212. Thus the automatic trunk hunting operation is initiated. This operation continues in the manner previously explained until an idle trunk circuit in the selected group is found or until all of the trunk circuits of the selected group have been tested and found to be occupied with calls. If all of the trunk circuits of the selected group are busy, the wipers 2341 to 2346, inclusive, are rotated to the eleventh rotary off-normal positions thereof, thereby to effect the energization of the test relay R2100, the transfer relay R2210 and the switching relay R2120 in the manner previously explained. The relays R2100 and R2120, in operating, open the circuit for energizing the rotary magnet 2260, thereby to arrest the rotary movement of the enumerated wipers. The switching relay R2120, upon operating, also short-circuits the test relay R2100 and deenergizes the two relays R2130 and R2140. Thus the three relays R2100, R2130 and R2140 are released, leaving only the two relays R2120 and R2210 operated in the selector 34. In this regard it will be noted that with the right normal post springs 2312 open, the relay R2310 cannot be energized. Thus the relay R2300 is prevented from operating to transmit to the preceding selector 32 the control signal which is required to cause this selector to insert the repeating coil 2020 in the connection and otherwise to prepare itself for the transmission of ringing current through the selector 34. It will also be noted that searching over a one digit level of the selector 34 during an interval when all of the trunks terminated in the level are busy does not result in the operation of the all-trunks-busy relay R2110. This is true for the reason that all the contacts engaged by the wiper 2343, during rotation of this wiper across a one digit level of contacts, are open-circuited. It will be noted further that since the repeating coil 2020 is not inserted in the connection between the trunk circuit 26 and the toll selector 34, and the relay R2300 is not operated, the switching relay R2120, upon operating to open the loop circuit extending from the trunk circuit 26 to the selector 34, disconnects both sides of this loop circuit from the negative terminal of the exchange battery. Thus no circuit is provided for energizing the simplex relay R680 of the trunk circuit 26 after this trunk circuit has shifted to its simplex pulse setting in the manner previously described. It

is noted, however, that the pulsing relay R680 is held energized through the contacts 671 of the simplex slave relay R670 and the contacts 321 of the signal relay R320. With the pulsing relay R680 operated, the hold relay R710 is energized through the contacts 662, thereby to prevent the trunk circuit 26 from attempting to release. When the trunk circuit 26 is shifted into its simplex pulse setting, a circuit is completed for transmitting ground pulses from the 120 I. P. M. lead C2637 through the upper winding of the supervisory relay R540, this circuit extending from the lead C2637 by way of the contacts 2115, the cam springs 2117, the contacts 2243, C2106, the wiper 2055, the contacts 1729 and 1939, the cam springs 1951, the contacts 1843, C1706, the wiper 1654, the contacts 1441 and 1449, C1338, the wiper 36d, C718, the contacts 446, and the upper winding of R540 to battery. The supervisory relay R540, in repeating the impulses to the signal lead C325, causes a flash busy signal to be produced by the supervisory lamp associated with the connection in the distant toll office No. 1. The speed of flashing, i. e., 120 flashes per minute, serves to inform the operator handling the call in this office that an all-busy condition has been encountered at a switching stage which precedes the final switching stage of the desired connection. Upon receiving this signal the operator handling the call may release the connection in the manner explained above.

Assuming now that the trunk circuit 4 is idle at the time the trunk hunting operation of the toll selector 34 is initiated, this trunk circuit may be seized through the outlet contacts of the selector. Thus when the wipers 2341 to 2346, inclusive, are rotated to engage the contacts terminating the conductors of the trunk 4f, the test relay R2100 is energized and operates to deenergize the rotary magnet 2260 and complete the operating circuit for the switching relay R2120. The latter relay, upon operating, switches the loop circuit through to the trunk circuit 4 and connects the test conductor of the trunk 4f to ground in a manner which will be clearly apparent from the preceding explanation. In this regard it will be noted that a loop circuit free of attachments is established between the trunk circuit 26 and the trunk circuit 4, incident to the operation of the switching relay R2120. This loop circuit includes the windings of the line relay conventionally provided in the trunk circuit 4 and the exchange battery. Thus the energization of the loop seizure relay R650 is sustained to prevent the trunk circuit 26 from shifting to its simplex pulse setting. When the test conductor of the trunk 4f is connected to ground and the loop circuit is extended to the trunk circuit 4, this trunk circuit is seized and is marked against seizure through the outlet contacts of the other toll selectors. Following the seizure of this trunk circuit, the connection may be extended through the automatic exchange 3 to the desired subscriber served by this exchange, in an entirely conventional manner. In this regard it will be noted that since the loop seizure relay R650 remains operated, the signal relay R320 and the pulsing relay R680 may continue to operate to transmit loop pulses to the trunk circuit 4 which are repeated through this trunk circuit to the automatic switching equipment in the exchange 3 for the purpose of directing the call to the desired line. It will also be observed that the E. C. control path as set up between the trunk circuit 26 and the selector 34 is extended 75 through this selector to the trunk circuit 4 over

a path which includes the contacts 2243 and 2121, and the wiper 2345. Accordingly, the trunk circuit 4 is rendered operative to transmit supervisory signals directly to the trunk circuit 26 wherein they may be repeated over the trunk 5 to the distant toll office No. 1. More specifically, when the call is extended to the called line in the automatic exchange 3 a signal is returned through the switch train in this exchange to the trunk circuit 4 which causes the trunk circuit to dry the loop circuit back to the trunk circuit 26. When the exchange battery is excluded from this loop circuit the trunk circuit 26 is shifted to its simplex pulse setting in the manner described above. Thereafter and when the call is answered at the called substation, an off-hook supervisory signal is transmitted to the trunk circuit 4. This trunk circuit responds to the signal by terminating the E. C. control path which extends through the selectors 31, 32 and 34 at ground, whereby the supervisory relay R540 is energized. This relay, in operating, transmits an off-hook supervisory signal over the signal lead C325 and the trunk 5 to the distant toll office No. 1. The arrangement of the supervisory relays in the trunk circuit 4 is such that these relays will respond to switchhook operations performed at the answering substation to repeat corresponding signals over the E. C. control path to the supervisory relay R540 in the trunk circuit 26. More specifically, each time the switchhook at the answering substation is operated to effect the transmission of an on-hook supervisory signal to the trunk circuit 4, the supervisory relays of this trunk circuit operate to disconnect the E. C. control path from ground and thus cause the deenergization of the supervisory relay R540. This relay, in releasing, transmits an on-hook supervisory signal to the operator handling the call in the distant toll office No. 1. Conversely, each time the answering subscriber operates the switchhook at the answering substation to re-establish the connection, an off-hook supervisory signal is transmitted to the trunk circuit 4. The supervisory relays in this trunk circuit respond to the off-hook supervisory signal by again connecting the E. C. control path to ground to effect the reoperation of the supervisory relay R540. This relay, in reoperating, again transmits an off-hook supervisory signal to the operator handling the call in the distant toll office No. 1. From this brief explanation it will be understood that when the called subscriber disconnects, a steady on-hook supervisory signal is produced by the supervisory lamp associated with the connection in the toll office No. 1 to inform the operator handling the call in this office that the switch train may be released. The manner in which the switch train including the trunk circuit 26, the link 35, the selector 32, and the selector 34 is released when the operator in the toll office No. 1 disconnects, is exactly the same as explained above. The trunk circuit 4 and the operated switch train in the distant automatic exchange 3 are released when the switching relay R2120 of the selector 34 opens its contacts 2129 to disconnect the test conductor of the trunk 4 from ground.

Routing the call to the toll office No. 2

The trunking plan of the central office 10 is such that all trunks accessible to the toll selector 32, with the exception of the trunks extending to the toll third selector, such, for example, as the selector 34, are reached through two digit contact levels of the toll selector 32 and the other

5 toll second selectors. Accordingly, if the above-described call originating in the toll office No. 1 and routed through the trunk circuit 26 and the link 35 to the selector 32 is to be extended to the toll office No. 2 for completion, two digits are required in the selector 32 in order to select the group of toll trunks extending to the toll office No. 2. The first of these digits is utilized in the manner described above to position the wipers 2051 to 2056, inclusive, opposite the level of bank contacts at which are terminated the trunk circuits associated with the inter-office trunks extending to the toll office No. 2. Immediately the enumerated wipers are moved to this vertical off-normal position, the right normal post springs 1915 are opened to interrupt the operating circuit for the relay R1910 and thus render the ringing facilities of the selector 32 inactive. The second digit transmitted to the toll selector 32 is utilized in the manner previously described to position the wipers 2051 to 2056, inclusive, on the contacts of the contact set terminating the trunk circuit associated with the first trunk of the desired group. It will be recalled that during this operation the relays R1820, R1830, R1840 and R1860 are held operated. It will also be recalled that after the second digit is ended, the relays R1830, R1820 and R1860 are successively released to initiate the automatic trunk hunting operation of the selector and that the relay R1840 is held operated until an idle trunk circuit in the selected group is found.

35 In this case, the wipers 2051 to 2056, inclusive, are positioned to select the first trunk of the desired group at the end of the second digit transmitted to the selector 32. The relay R1820, upon restoring at the end of the digit, completes the prepared operating circuit for the relay R1900. In this regard it is noted that the contacts adapted to be engaged by the wiper 2056 during trunk hunting over a trunk group of the character under consideration, are connected to ground. Accordingly, the operating circuit for the relay R1900 may be traced as extending from the 40 grounded wiper 2056 by way of the contacts 1945, 1933, 1904, 1845, 1716 and 1827, and the winding of R1900 to battery.

45 In operating, the relay R1900 locks to the grounded test conductor C1705 through its preliminary make contacts 1901 and then opens its operating circuit at the contacts 1904. At its contacts 1903, the relay R1900 opens another point in the operating circuit for the relay R1910. At its contacts 1902, the relay R1900 connects the 50 E. C. trunk conductor C1706 through the resistor 1906 to the negative terminal of the exchange battery, thereby to provide a circuit for energizing the transfer relay R550. The current flow over this circuit is of sufficient magnitude to 55 cause the operation of the relay R550. This relay, in operating, closes its contacts 551 to complete an obvious circuit for energizing the slow-acting transfer slave relay R560. The relay R560 now operates and closes its contacts 561 to complete an obvious circuit for energizing the supervisory relay R540. The relay R540, in operating, opens its contacts 544 and closes its contacts 543, whereby negative battery potential is substituted for ground potential upon the signal lead C325 and the two conductors of the trunk 5. The negative potential thus applied to the two conductors of the trunk 5 constitutes a stop-in-dial or delay send signal which is utilized by the switching equipment in the distant toll office No. 1 either to inform the operator handling the call

that the dialing operation should be arrested or directly to control the register sender associated with the connection in this office so that the transmission of impulses therefrom is stopped. The purpose of transmitting this signal is to prevent the impulses of the next digit from being transmitted to the trunk circuit 26 until this trunk circuit, a succeeding trunk circuit, and the toll switching equipment in the toll office No. 2 are fully conditioned to accept the incoming switch directing pulses.

Further to consider the manner in which the call is extended to the toll office No. 2, it may be assumed that the trunk 27f extending to the trunk circuit 27 is seized during the trunk hunting operation of the selector 32. The manner in which this seizure is effected is exactly the same as explained above, it being noted in this regard that when the switching relay R1720 operates, it opens its contacts 1725 to deenergize the relay R1840. The latter relay, upon restoring, opens its contacts 1842 to interrupt the circuit through the resistor R906 for energizing the transfer relay R550, and closes its contacts 1843 to prepare a circuit including the E. C. control path for energizing the transfer relay R550 in series with the two switching relays R950 and R960 in the manner explained below. The remaining circuit switching operations performed by the relay R1840 are without effect. In operating to switch the connection through to the trunk circuit 27, the relay R1720 also completes a path through the contacts 1727, 1816, 1713, 1825 and 1833, and the wiper 2053 for connecting the test conductor C1279 of the trunk 27f to ground. At its contacts 1722 and 1724, the relay R1720 also extends the loop circuit from the trunk circuit 26 to the trunk circuit 27. Following the switch-through operation of the selector 32 only the relays R1720 and R1900 are operated therein.

When the test conductor C1279 of the trunk 27f is connected to ground in the selector 32, a circuit including this conductor and the contacts 1261 and 1224 is completed for energizing the seizure relay R1140 of the trunk circuit 27. This relay, in operating, closes its contacts 1141 to energize the switching relay R1130, and closes its contacts 1143 to prepare locking circuits for the two switching relays R930 and R940. At its contacts 1144, the relay R1140 opens a point in the operating circuit for the relay R920. At its contacts 1145, the relay R1140 opens a point in the operating circuit for the seizure relay R1260, thereby to prevent the trunk circuit 27 from being seized at the toll switchboard 30. At its contacts 1142, the relay R1140 extends the E. C. control path, originating in the trunk circuit 26, to ground through the contacts 1072, 912 and 948, thus providing a path over which the transfer relay R550 is momentarily short-circuited. At its contacts 1141, the relay R1140 also completes an obvious circuit for energizing the control relay R1030. The latter relay, upon operating, closes its contacts 1031 to complete a circuit for energizing the relay R920, this circuit extending from ground by way of the contacts 1163, 932' and 1031 and the winding of R920 to battery.

The relay R920, upon operating, closes its contacts 922 to prepare a locking circuit for itself and, at its contacts 921', short-circuits the repeating coil winding 813. At its contacts 921, the relay R920 opens a point in the operating circuit for the supervisory relay R910. At its contacts

923, the relay R920 opens a point in the locking circuit for the relay R1240.

The switching relay R1130, upon operating, closes its contacts 1136' to complete an obvious path for connecting the signal lead C1142 to ground, whereby the busy signal lamps individual to the trunk circuit 27 and provided at the toll switchboard 30 are energized to indicate that the trunk circuit 27 is occupied with a call. 5 At its contacts 1135', the relay R1130 prepares another operating circuit for the digit relay R920. At its contacts 1131, the relay R1130 opens the path including the contacts 1041 and the two conductors C841 and C842 over which the terminating impedance 844, 845 is normally bridged across the talking conductors connecting the two repeating coils 804 and 810. At its contacts 1132 and 1134, the relay R1130 disconnects the repeating coil 810 from the talking conductors C1275 and C1276 of the trunk 27d extending to the banks of the finder 36. At its contacts 1136 and 1138, the relay R1130 opens two points in the operating circuit for the simplex relay R1180. At its contacts 1138, the relay R1130 also opens a point in the operating circuit for the pulsing relay R1160. At its contacts 1131' and 1133', the relay R1130 opens the path over which the operating winding of the loop seizure relay R1150 may be bridged across the talking conductors C1275 and C1276 in response to seizure of the trunk 6 in the distant toll office No. 2. At its contacts 1133 and 1135, the relay R1130 connects the repeating coil 810 to the talking conductors C1148 and C1146 of the trunk 27f. At its contacts 1137, the relay R1130 prepares the operating circuit for the simplex pulsing relay R1080. At its contacts 1139, the relay R1130 prepares the operating circuit for the supervisory relay R910. At its contacts 1132' 30 and 1134', the relay R1130 inserts the windings of the loop pulse relay R1110 and the differential relay R1120 in the loop circuit connecting the trunk circuit 26 with the trunk circuit 27. More specifically, with the switching relay R1130 operated, the loop circuit extends from ground by way of the upper winding of R1110, the upper winding of R1120, the contacts 1132' and 932, the winding 814, the contacts 1135 and 1274, C1146, the wiper 2052, the contacts 2034, 1934 45 and 1724, C1704, the wiper 1652, the contacts 1445 and 1444, C1336, the wiper 36b, C776, the contacts 634, the winding 314, the contacts 432, 631' and 661, the lower winding of R650, the contacts 633' and 434, the winding 313, the contacts 632, C775, the wiper 36a, C1335, the contacts 1412 and 1441, the wiper 1651, C1703, the contacts 1722, 1931 and 2031, the wiper 2051, C1148, the contacts 1272 and 1133, the winding 813, the contacts 934 and 1134', the lower winding 50 of R1120, the contacts 936 and 1021, and the lower winding of R1110 to battery. It will be noted from the preceding explanation that initially the positive side of the above-traced loop circuit is connected to ground in the trunk circuit 26 over a path which includes the contacts 661, 651, 733, 742 and 662. Accordingly, the upper windings of the two relays R1110 and R1120 are short-circuited immediately the connection is switched through to the trunk circuit 27. This 55 permits the differentially wound relay R1120 to operate without interfering with the operation of the loop pulse relay R1110. In other words, both of these relays operate when the connection is switched through to the trunk circuit 27 from the trunk circuit 26.

The loop pulse relay R1110, upon operating, closes its contacts 1111 to short-circuit the control relay R1030, whereby the latter relay and the relay R920 are sequentially released in the order named. At its contacts 1113, the relay R1110 disconnects the signal lead C1025 from ground. At its contacts 1112, the relay R1110 connects the signal lead C1025 to the negative terminal of the exchange battery over a path which includes the resistor 1101 and the contacts 1112, 1083 and 1075.

The differential relay R1120, upon operating, closes its contacts 1071 to complete an obvious circuit for energizing its slave relay R1070. The relay R1070, in operating, closes its contacts 1071 to prepare a locking circuit for itself. At its contacts 1074 and 1075, the relay R1070 first completes an obvious multiple path for impressing negative battery potential upon the signal lead C1025, and then opens the initially completed path over which this lead is connected to the negative terminal of the exchange battery. At its contacts 1072, the relay R1070 disconnects the E. C. control path from ground in the trunk circuit 27, thereby to open the short circuit across the winding of the transfer relay R550. At its contacts 1073, the relay R1070 connects the E. C. control path to the negative terminal of the exchange battery through the series-connected windings of the two control relays R960 and R950. Thus a circuit is completed for energizing the two enumerated control relays and the transfer relay R550 in series. The windings of the two relays R960 and R950 are of relatively low resistance, being of the order of 25 ohms and 450 ohms, respectively. Accordingly these two relays and the transfer relay R550 all operate when the described series energizing circuit is completed. At this point it is noted that the period required to effect the operation of the four relays R1140, R1130, R1120 and R1070 in the manner just explained is less than the combined release periods of the two relays R550 and R560. Accordingly, the supervisory relay R540 is prevented from releasing to terminate the above-described stop-in-dial signal, during the interval required to transfer the E. C. control path from a connection to battery in the selector 32 to a connection to battery in the trunk circuit 27. The control relay R950, upon operating in the trunk circuit 27, closes its contacts 951 to complete an obvious circuit for energizing the switching relay R940. The relay R960, upon operating, closes its contacts 961 to prepare the operating circuit for the switching relay R930. At its contacts 962, the relay R960 completes an obvious operating circuit for the control relay R970.

The relay R940, upon operating, locks to ground through the contacts 949 and 1143, and opens its contacts 948 to interrupt the path for impressing ground potential upon the E. C. conductor C1280. At its contacts 947, the relay R940 prepares an alternative ground termination for the indicated E. C. conductor. At its contacts 945, the relay R940 disconnects the E. C. conductor C1278 from the transfer relay R1050. At its contacts 946, the relay R940 connects the E. C. conductor C1278 to the upper winding of the supervisory relay R1040. At its contacts 944, the relay R940 opens a point in the available holding circuit for the loop pulsing relay R1110. At its contacts 941 and 943, the relay R940 prepares a path for conductively connecting the inner terminals of the repeating coil windings 813 and 814 in order to establish a simplex

75 pulsing circuit between the two trunk circuits 26 and 27 in the manner pointed out below. At its contacts 942, the relay R940 opens a point in the operating circuit for the rering relay R980.

The relay R970, upon operating, closes its contacts 971 to complete the prepared locking circuit for the differential slave relay R1070. At its contacts 972, the relay R970 opens a point in the path for conductively connecting the inner terminals of the repeating coil windings 813 and 814. At its contacts 973, the relay R970 completes the prepared operating circuit for the switching relay R930. At its contacts 974, the relay R970 prepares a locking circuit for the supervisory relay R1040.

The relay R930, upon operating, locks to ground through the contacts 931' and 1143, and closes its contacts 938 further to prepare the path for impressing ground potential upon the E. C. conductor C1280. At its contacts 932', the relay R930 opens another point in the above-traced operating circuit for the relay R920. At its contacts 939, the relay R930 opens a point in one of the operating circuits for the two control relays R950 and R960. At its contacts 937, the relay R930 opens a point in the path for impressing negative battery potential upon the E. C. conductor C1280. At its contacts 935, the relay R930 prepares the above-mentioned holding circuit for the loop pulse relay R1110. At its contacts 931 and 933, the relay R930 further prepares the above-mentioned path for conductively connecting the inner terminals of the repeating coil windings 813 and 814. At its contacts 932, 934 and 936, the relay R930 opens three points in the loop circuit as established between the trunk circuit 26 and the trunk circuit 27, and in so doing interrupts the path short-circuiting the upper windings of the relays R1110 and R1120. It will be understood in this regard that when the indicated loop circuit is opened, the three relays R650, R1110 and R1120 are all de-energized and restore.

When the loop seizure relay R650 releases in the trunk circuit 26, this trunk circuit is shifted to its simplex pulse setting in the exact manner explained above. From this explanation it will be recalled that to shift the control equipment of the trunk circuit 26 from its loop pulse setting to its simplex pulse setting, the relays R450, R460, R470, R430 and R440 are operated in response to the release of the loop seizure relay R650, following which the three control relays R450, R460 and R470 are deenergized under the control of the switching relay R430. With the two switching relays R430 and R450 operated, a simplex circuit is prepared for energizing the simplex relay R680 in series with the simplex pulsing relay R1080 of the trunk circuit 27, this simplex circuit being completed in the trunk circuit 27 in the manner explained below. In this case, the relay R440, upon opening its contacts 445, deenergizes the transfer relay R550 causing the latter relay to restore. In releasing, the relay R550 opens its contacts 551 to deenergize the transfer slave relay R560. The latter relay, upon restoring, opens its contacts 561 to interrupt the above-described operating circuit for the supervisory relay R540. It is noted, however, that this supervisory relay is locked energized through the contacts 542 and 474 until the control relay R470 is released at the end of the transfer operation. When this locking circuit is opened at the contacts 474, the supervisory relay R540 opens its contacts 543 and closes its contacts 544, thereby

to substitute ground potential for negative battery potential upon the signal lead C1025. This change in the character of the potential applied to the lead C1025 marks the termination of the stop-in-dial signal being transmitted to the equipment occupied with the call in the distant toll office No. 1, whereby this equipment is conditioned to transmit the remaining digits of the directory number to the trunk circuit 26.

When deenergized in the manner explained above, the differential relay R1120 opens its contacts 1121 to interrupt the operating circuit for the differential slave relay R1070. The loop pulse relay R1110 restores coincident with the release of the relay R1120 and opens its contacts 1111 to interrupt the path short-circuiting the winding of the control relay R1030. At its contacts 1112, the relay R1110 opens a point in one of the paths for impressing negative battery potential upon the signal lead C1025. At its contacts 1113, the relay R1110 prepares a path for impressing ground potential upon the signal lead C1025.

The control relay R950, upon restoring in response to the operation of the switching relay R440, opens its contacts 951 to interrupt the operating circuit for the switching relay R940. The control relay R960, in releasing, opens its contacts 961 to interrupt the operating circuit for the switching relay R930. At its contacts 962, the relay R960 deenergizes the control relay R970. The relay R970 now restores and opens its contacts 971 to deenergize the differential slave relay R1070. At its contacts 973, the relay R970 opens another point in the operating circuit for the switching relay R930. At its contacts 974, the relay R970 opens the prepared locking circuit for the supervisory relay R1040. At its contacts 972, the relay R970 completes the above-mentioned simplex circuit for energizing the simplex pulsing relay R1080 in series with the simplex relay R680 of the trunk circuit 26. One branch of this circuit may now be traced as extending from ground by way of the contacts 321 and 638, the winding of R680, the contacts 636, 441 and 431, the winding 314, the contacts 634, C776, the wiper 36b, C1336, the contacts 1414 and 1445, the wiper 1652, C1704, the contacts 1724, 1934 and 2034, the wiper 2052, C1146, the contacts 1274 and 1135, the winding 814, the contacts 931, 941 and 1137, and the winding of R1080 to battery. It will be noted that this branch of the simplex circuit is completed independently of the contacts 972 immediately the trunk circuit 26 is shifted to its simplex pulse setting. The other branch of the simplex circuit extends from ground by way of the contacts 321 and 638, the winding of R680, the contacts 636, 472, 443 and 433, the winding 313, the contacts 632, C775, the wiper 36a, C1335, the contacts 1412 and 1441, the wiper 1651, C1703, the contacts 1722, 1931 and 2031, the wiper 2051, C1148, the contacts 1272 and 1133, the winding 813, the contacts 933, 943, 972 and 1137, and the winding of R1080 to battery. When energized in this circuit the relays R1080 and R680 both operate. Upon operating, the relay R1080 closes its contacts 1081 to short-circuit the winding of the control relay R1030 and thus prevent this relay from reoperating. At its contacts 1082, the relay R1080 prepares an alternative path for connecting the signal lead C1025 to the negative terminal of the exchange battery. At its contacts 1083, the relay R1080 opens a point in one of the

paths over which this signal lead may be connected to ground in the trunk circuit 27.

The differential slave relay R1070 restores shortly following the operation of the simplex pulsing relay R1080, and opens its contacts 1073 further to interrupt the above-traced circuit for energizing the two relays R950 and R960 in series with the transfer relay R550. At its contacts 1072, the relay R1070 prepares paths for transmitting supervisory signals over the E. C. control path extending to the trunk circuit 26. At its contacts 1074 and 1075, the relay R1070 first closes a path through the contacts 1082 for maintaining negative battery potential upon the signal lead C1025, and then opens the path for directly connecting the signal lead to the negative terminal of the exchange battery. Following the relay operations just described the trunk circuit 27 is conditioned to respond to impulses transmitted thereto from the trunk circuit 26.

The simplex relay R680 of the trunk circuit 26, upon operating, closes its contacts 681 to energize the slow-acting simplex slave relay R670. The latter relay, upon operating, closes its contacts 672 to complete a multiple circuit for energizing the hold relay R710, and opens its contacts 671 to deenergize the pulsing relay R660. The relay R660 now restores and opens its contacts 662 to interrupt the operating circuit for the hold relay R710. At its contacts 661, the relay R660 opens another point in the incomplete path for bridging the operating winding of the loop seizure relay R650 across the talking conductors C175 and C176. At its contacts 663, the relay R660 reprepares the above-traced operating circuit for the digit relay R730 and prepares one of the operating circuits for the relay R420.

When negative battery potential is applied to the two conductors of the trunk 6 over the signal lead C1025 in the manner explained above, the trunk circuit terminating this trunk in the distant toll office No. 2 operates to effect the extension of the connection either directly or indirectly to a toll preselector in this toll office. Incident to this operation, the seized toll preselector is conditioned to respond to impulses transmitted thereto from the trunk circuit terminating the trunk 6 in the toll office No. 2, and the trunk circuit is conditioned to perform the required impulse repeating operations. These operations are all effected in the toll office No. 2 during the interval when the stop-in-dial signal is transmitted to the toll office No. 1, so that by the time the stop-in-dial signal is terminated, the seized equipment in the toll office No. 2 is fully conditioned to accept switch directing impulses. In this regard it will be noted that when the dialing operation is resumed in the toll office No. 1, the signal relay R320 functions to repeat the received dial impulses to the series-connected simplex relays R680 and R1080. The relay R680 responds by repeating the impulses to the simplex slave relay R670. The latter relay, due to its slow-to-release characteristic, remains operated during this impulse repeating operation.

Each time the contacts 321 are opened to deenergize the simplex pulsing relay R1080, this relay opens its contacts 1082 to disconnect the signal lead C1025 from the negative terminal of the exchange battery, and closes its contacts 1083 to connect the signal lead to ground over a path which includes the additional contacts 1075, 1113 and 1044. In releasing, the relay R1080 also opens its contacts 1081 to interrupt the path short-circuiting the winding of the control relay R1030,

effect a closing of bus 66501 which blocks out the path permitting the latter relay to reoperate. Conversely, each time the relay R1080 reoperates at the end of the open-circuit period of an impulse, it substitutes negative battery potential for ground potential on the signal lead C1025 and recloses its contacts 1081 to short-circuit the control relay R1030. Thus it will be noted that the relay R1030 is also controlled to follow the impulses repeated to the trunk circuit 27 from the trunk circuit 26. This relay, in reoperating at the beginning of the open-circuit period of the first impulse in each digit transmitted to the trunk circuit 27, closes its contacts 1031 to prepare the above-traced operating circuit for the relay R820. This circuit, however, is held open at the contacts 932' of the operated switching relay R930 so that the relay R820 is prevented from responding to the operation of the control relay R1030.

As indicated by the above explanation, the impulses repeated by the trunk circuit 26 to the trunk circuit 27 are in turn repeated by the simplex pulsing relay R1080 over the signal lead C1025 and the two conductors of the trunk 6 in the form of alternate battery and ground pulses. More specifically, the open-circuit period of each dialed impulse is represented by a ground pulse on the conductors of the trunk 6, whereas the closed-circuit period of each dialed impulse is represented by a negative battery pulse on the two conductors of the trunk 6. These alternate pulses of ground and battery potentials as received by the trunk circuit terminating the trunk 6 in the distant toll office No. 2, are repeated from this trunk circuit to the succeeding switching equipment for the purpose of routing the call to the desired destination in this office. In this regard it is noted that after the impulse transmitting operation is completed, no further relay operations occur in either of the two trunk circuits 26 and 27 until an answer supervisory signal is transmitted over the trunk 6 from the terminating trunk circuit in the distant toll office No. 2. When the call is answered at the toll switchboard or a substation in the distant toll office No. 2, negative battery potential is impressed upon the two conductors of the trunk 6 in the trunk circuit which terminates this trunk in the distant toll office. In response to this operation, the signal relay R820 operates and closes its contacts 821 to complete a circuit through the contacts 1139 and 921 for energizing the supervisory relay R910. The relay R910, upon operating, closes its contacts 913 to prepare a multiple circuit for energizing the switching relay R930. At its contacts 911, the relay R910 connects the E. C. control path to ground through the contacts 1142, 1072, 938 and 947, thereby to provide a circuit for energizing the supervisory relay R540. In operating, the relay R540 substitutes negative battery potential for ground potential upon the signal lead C325, thereby to transmit an off-hook supervisory signal to the operator handling the call in the distant toll office No. 1. From the above explanation, it will be understood that if the call is extended to the toll switchboard in the toll office No. 2 and the operator handling the call in this office desires to resign the operator handling the call in the toll office No. 1, she may, by key operations or otherwise, cause the two sides of the trunk 6 to be intermittently connected to ground and the negative terminal of the battery provided in the toll office No. 2, thereby to cause the intermittent operation of the three relays R820, R910 and R540. These relays will also follow switchhook operations at the called substation served by the

75 two distant toll offices 3 off office No. 2 and work toll office No. 2. The last of these relays, i. e., the relay R540, in operating and restoring, functions to transmit a flashing recall supervisory signal to the operator handling the call in the toll office No. 1. It will also be understood that when the operator handling the call in the toll office No. 2 disconnects, the relays R320, R910 and R540 are successively released and remain in their respective restored positions, whereby a steady on-hook supervisory signal is transmitted to the operator handling the call in the toll office No. 1.

If the connection is extended to the toll switchboard in the toll office No. 2 and the operator handling the call in the toll office No. 1 desires to resign the called operator, she may, by key operations or otherwise, transmit a 50-120 millisecond ground pulse over the two sides of the trunk 5 for the purpose of effecting the sequential release of the two relays R320 and R1080 in a manner clearly apparent from the above explanation. The simplex relay R680 and its slave relay R610 may also be released during the recall interval, but the release of these two relays is without effect. Moreover, the relay R1080 may also be operated without effect during the recall interval. The simplex pulsing relay R1080, upon restoring, substitutes ground potential for negative battery potential upon the signal lead C1025, thereby to transmit an on-hook supervisory signal to the operator handling the call in the distant toll office No. 2. The termination of this signal as effected by the reoperation of the relays R320 and R1080 at the end of the signal period, serves to inform the operator handling the call in the toll office No. 2 that she is being recalled from the calling toll office No. 1.

The release of the connection as completed through the switching equipment of the central office 10 between the two offices is entirely under the control of the operator handling the call in the toll office No. 1. More specifically, when the calling operator in the toll office No. 1 takes down the connection the signal relay R320 is deenergized and restores to effect the release of the trunk circuit 26, the link 35, and the selector 32, in the exact manner previously explained. This relay, in releasing, also deenergizes the simplex pulsing relay R1080, whereby a steady on-hook supervisory signal is transmitted to the distant toll office No. 2, assuming that the connection has not previously been released in this office. Incident to the release of the selector 32, and more specifically when the switching relay R1720 restores, the test conductor C1279 of the trunk 27 is disconnected from ground to deenergize the seizure relay R1140. In releasing, the relay R1140 opens its contacts 1141 to deenergize the switching relay R1139 and to open the circuit for energizing the control relay R1030. At its contacts 1143, the relay R1140 deenergizes the two operated switching relays R930 and R940. Following the release of the six relays R1080, R1140, R1130, R1030, R940 and R930 the trunk circuit 27 is fully restored to normal and is rendered available for further use. In this regard it will be noted that when the test conductor C1279 is disconnected from ground in the selector 32, this conductor is marked with negative battery potential through the winding of the seizure relay R1140 to identify the trunk circuit 27 as idle in the bank contacts of the toll selectors to which it is accessible.

75 The manner in which a call may be routed

from the toll office No. 2 through the trunk circuit 27, the link 35, the selector 32, and the trunk circuit 26 to a desired destination in the toll office No. 1 is in all respects the same as that just described with reference to the extension of a connection in the reverse direction, i. e., from the toll office No. 1 to the toll office No. 2. In this regard it is noted that the two trunk circuits 26 and 27 are in all respects identical. Accordingly, the above explanation with reference to a connection utilizing the two trunk circuits in tandem adequately covers all conditions which arise in these two trunk circuits, regardless of the direction in which a particular call proceeds between the indicated toll offices.

Routing the call to the toll operator switchboard 11

If the above-described call originating in the toll office No. 1 and routed through the trunk circuit 26 and the link 35 to the toll selector 32 is to be extended to the toll operator switchboard 11 in the central office 10, either a trunk circuit of the inward group, including the trunk circuit 25, or one of the inter-position trunk circuits, such, for example, as the trunk circuit 24, may be seized through the outlet contacts of the selector 32. In this case two digits are required in the toll selector 32 in order to select the desired group of trunks, and the right normal post springs 1915 are operated at the end of the first digit to render the ringing equipment of the selector 32 inactive. These operations, as well as that of switching the connection through to a selected trunk circuit are all accomplished in the exact manner explained above with reference to the extension of a connection to the toll office No. 2. If the second digit dialed into the selector 32 designates the group of inward trunk circuits, it may be assumed that the trunk circuit 25 is seized during the trunk hunting operation of the selector 32. Incident to the seizure of this trunk circuit, the rotary position thereof is marked in the banks of the answer switches associated with the switchboard 11, and a marking path is completed to the common start circuit 12 which indicates that the trunk circuit 25 is occupied with a call.

More specifically, when the trunk circuit 25 is seized through the outlet contacts of the selector 32, the switching relay R1720 operates in this selector to connect the talking conductors C1703 and C1704 by way of the talking wipers 2051 and 2052 and the talking conductors C2331 and C2332 to one side of the repeating coil 2383. Incident to this operation the lower winding of the loop seizure relay R650 is momentarily energized in series with the winding of the relay R2365 over a circuit which will be clearly apparent from the preceding explanation. In operating, the switching relay R1720 also connects the test conductor C2333 to ground in the selector 32, thereby to provide a circuit through the contacts 2392 and 2376 for energizing the seizure relay R2370. In operating, the switching relay R1720 also effects the release of the relay R1840 in the manner previously explained. The latter relay, upon restoring, closes its contacts 1843 to connect the two E. C. conductors C1706 and C2334 together and thus provide a circuit through the winding of the transfer relay R550 for energizing the relay R2368. The resistance of this circuit is such that the relay R550 does not operate when energized therein.

The relay R2370, upon operating, closes its contacts 2371 to prepare the operating circuit for

the cut-off relay R2390 and to provide a resistance battery marking path which includes the upper winding of the cut-off relay R2390 and the test conductor 25c for marking the rotary position of the trunk circuit 25 in the banks of the answer switches associated with the switchboard 11. At its contacts 2372, the relay R2370 prepares a locking circuit for the relay R2350. At its contacts 2373, the relay R2370 connects the start lead C2859 to ground, thereby to mark the trunk circuit 25 as a calling trunk circuit in the common start circuit 12. The relay R2360, upon operating, opens its contacts 2381 to interrupt one side of the available simplex circuit for energizing the relay R2365 in series with the simplex relay R680 of the trunk circuit 26. At its contacts 2382, the relay R2360 opens a point in the operating circuit for the relay R2350.

When the negative talking lead C2331 is disconnected from the negative terminal of the exchange battery at the contacts 2381, the loop seizure relay R650 of the trunk circuit 26 is de-energized and restores. This relay, in releasing, causes the control equipment of the trunk circuit 26 to be shifted to its simplex pulse setting in the exact manner previously explained. Incident to this operation, the simplex relay R680 is energized in series with the relay R2365 over the positive side of the connection extending between the trunk circuit 26 and the trunk circuit 25. Also incident to the operation of the trunk circuit 26 to its simplex pulse setting, the switching relay R440 is operated to open its contacts 445 and thus deenergize the relay R2360.

The relay R2360, upon restoring, closes its contacts 2361 to complete the other side of the simplex circuit over which the relay R2365 is energized in series with the simplex relay R680 of the trunk circuit 26. At its contacts 2362, the relay R2360 closes a point in the operating circuit for the relay R2350. The relay R2365 operates when energized in series with the simplex relay R680 and closes its contacts 2366 to complete the prepared operating circuit for the relay R2350. At its contacts 2367, the relay R2365 prepares a holding circuit for the relay R2390.

The relay R2350, upon operating, opens its contacts 2351 to interrupt the available path for connecting the test conductor C2333 to ground. At its contacts 2352, the relay R2350 prepares the operating circuit for the relay R2375. At its contacts 2353, the relay R2350 opens another point in the operating circuit for the relay R2360. At its contacts 2354, the relay R2350 prepares a path for connecting the E. C. conductor C2334 to ground. At its contacts 2355, the relay R2350 locks to ground through the contacts 2372.

When the start lead C2859 is connected to ground through the contacts 2373 to mark the trunk circuit 25 in the common start circuit 12 as being occupied with a call, the assigned answer switch associated with the operator position which is allotted by the position distributor 13 to handle the call, is operated to seize the trunk circuit 25. For explanatory purposes, it may be assumed that the call is extended to the first position of the switchboard 11 through the answer switch 16. In this regard it will be recalled that when the answer switch 16 functions to seize the trunk circuit 25 and thus extend the connection to the position circuit 18, the switching relay R2460 operates to connect the test conductor 25c to ground over a path which includes the lower winding of the supervisory relay R2820 and the contacts 2484. Thus a circuit including

from the start relay **R250** through contacts **2371** and **2372** to the test conductor **25c** and the contacts **2371** is completed for energizing the upper winding of the cut-off relay **R2390**. In operating, the relay **R2390** closes its preliminary make contacts **2395** to complete a locking circuit for itself which includes the grounded test conductor **25c**, the resistor **2396** and its two windings in series. At its contacts **2381**, the relay **R2390** opens the path over which the terminating impedance **2397, 2398** is normally bridged across the talking conductors **25a** and **25b**. At its contacts **2392**, the relay **R2390** deenergizes the seizure relay **R2370**. At its contacts **2393**, the relay **R2390** completes a circuit including the grounded test conductor **C2333** and the contacts **2352** for energizing the relay **R2375**. At its contacts **2394**, the relay **R2390** completes a path through the contacts **2381** and **2354** for impressing ground potential upon the E. C. conductor **C2334**. When this conductor is connected to ground, the supervisory relay **R540** is energized over the E. C. control path as set up between the two trunk circuits **26** and **25**. In operating, this relay transmits an off-hook supervisory signal to the operator handling the call in the distant toll office No. 1 in the exact manner previously described. Thus the originating operator is informed that the call has been extended to the toll switchboard **11** in the central office **10**.

The relay **R2375**, upon operating, locks to the grounded test conductor **C2333** through its contacts **2377**. At its contacts **2376**, the relay **R2375** opens another point in the operating circuit for the seizure relay **R2370**. At its contacts **2378**, the relay **R2375** short-circuits the lower winding of the cut-off relay **R2390** and the resistor **2396**, thus excluding these two circuit elements from the circuit over which the lower winding of the supervisory relay **R520** is energized. At its contacts **2379**, the relay **R2375** completes a multiple holding circuit for the relay **R2350**.

The seizure relay **R2370**, upon restoring, opens its contacts **2371** to interrupt the above-described path for marking the rotary position of the trunk circuit **25** in the banks of the answer switches and to interrupt the circuit over which the cut-off relay **R2390** was initially energized. At its contacts **2372**, the relay **R2370** opens the initially completed locking circuit for the relay **R2350**. At its contacts **2373**, the relay **R2370** disconnects the start lead **C2859** from ground in the trunk circuit **25**, whereby this trunk circuit is no longer marked as being occupied with an unanswered call in the common start circuit **12**.

After the connection has been extended to the No. 1 position of the toll switchboard **11** in the manner just explained, the originating operator in the toll office No. 1 may converse with the answering operator attending the No. 1 position of the switchboard **11** and instruct the answering operator as to the name or directory number of the desired party. Upon receiving this information the answering operator at the No. 1 position of the switchboard **11** may extend the call to the desired destination through the call switch **17** in the manner previously explained. From this explanation, it will be recalled that after the connection has been extended to the desired substation and the operator handling the call at the No. 1 position of the switchboard **11** has released her position circuit **18** for use in handling other calls, the start relay **R2530** is deenergized so that a circuit through the contacts **2352** and controlled by the supervisory relay **R2520**, is prepared for controlling the energization of the rear super-

visor lamp **2603**. Normally, i.e., so long as the connection is not interrupted at the toll switchboard in the toll office No. 1, the relays **R2365** and **R2375** are held operated in the trunk circuit **25** to prevent the release of the supervisory relay **R2520**. Accordingly, the rear supervisory lamp **2603** is normally deenergized.

If the operator handling the call in the toll office No. 1 desires to resignal the operator attending the No. 1 position of the switchboard **11**, she may, by key operations or otherwise repeatedly disconnect the two sides of the trunk **5** from the negative terminal of the battery in the toll office No. 1, thereby to cause the repeated release and reoperation of the signal relay **R320**. Each time this relay restores it opens its contacts **321** to deenergize the simplex relay **R680**, the pulsing relay **R660** and the line relay **R2365** in the trunk circuit **25**. The momentary release of the two relays **R660** and **R680** and the possible release of the simplex slave relay **R670** are without effect. The relay **R2365**, upon restoring, opens its contacts **2367** to interrupt a path short-circuiting the resistor **2396** and the lower winding of the cut-off relay **R2390**, permitting these two elements to be serially included in the circuit for energizing the lower winding of the supervisory relay **R2520**. The decrease in current flow through the windings of the relay **R2390** is insufficient to effect the release of this relay. The decrease in current flow through the lower winding of the relay **R2520** is, however, sufficient to cause this supervisory relay to restore. In releasing, the relay **R2520** closes its contacts **2521** to complete the previously traced circuit for energizing the rear supervisory lamp **2603**. It will be understood that each time the signal relay **R320** is reoperated at the end of a signaling period, the relay **R2365** recloses its contacts **2367** to exclude the lower winding of the relay **R2390** and the resistor **2396** from the circuit for energizing the supervisory relay **R2520**. When the current flow through the lower winding of the relay **R2520** is thus increased, this relay re-operates and opens its contacts **2521** to deenergize the rear supervisory lamp **2603**. Thus if the signal relay **R320** is controlled intermittently to operate, the lamp **2603** is flashed to inform the operator attending the No. 1 position of the switchboard **11** that she is being recalled from the distant toll office No. 1.

If the operator attending the No. 1 position of the switchboard **11** desires to resignal the calling operator in the toll office No. 1, she must first operate the talk key **2550** for the purpose of reconnecting her position circuit **18** to the link **15**, and then repeatedly operate the ring key **4040** for the purpose of transmitting splashes of ringing current through the winding of the rering relay **R2380**. More specifically, this relay is energized in a circuit which includes the talking wiper **2401**, the talking conductor **25a**, the repeating coil winding **2386**, and the condenser **2382**, each time the ringing key **4040** is operated. In operating, the relay **R2380** opens its contacts **2381** to disconnect the E. C. control path from ground in the trunk circuit **25** and thus effect the release of the supervisory relay **R540** in the trunk circuit **26**. In restoring, the relay **R540** functions to transmit an on-hook supervisory signal to the operator handling the call in the toll office No. 1. Obviously the rering relay **R2380**, upon restoring at the end of each ringing interval, closes its contacts **2381** to re-energize the supervisory relay **R540**, whereby an off-hook supervisory signal is transmitted to the calling operator in the toll office No. 1. Thus

the supervisory relay R540, in following the operation of the rering relay R2380, functions to transmit a flashing recall signal to the operator handling the call in the distant toll office No. 1.

The release of the connection as set up through the trunk circuit 26, the link 35 and the selector 32, is under the control of the operator handling the call in the distant toll office No. 1 and is effected in the exact manner previously explained. The release of the link 15 occupied with the call at the switchboard 11 is under the control of the operator attending the No. 1 position of this switchboard and is also effected in the manner previously explained. The trunk circuit 25 is only released when both operators disconnect. Thus if the connection is released in the toll office No. 1 before it is released at the switchboard 11, the two relays R2365 and R2375 are deenergized in the trunk circuit 25 in an obvious manner in response to the release of the trunk circuit 26 and the selector 32. The relay R2365, upon restoring, opens its contacts 2366 to interrupt the operating circuit for the relay R2350. At its contacts 2367, the relay R2365 serially includes the lower winding of the cut-off relay R2390 and the resistor 2396 in the circuit for energizing the supervisory relay R2520. The relay R2375, upon restoring, closes its contacts 2376 to reprepare the operating circuit for the seizure relay R2370. At its contacts 2377, the relay R2375 opens a point in its own locking circuit. At its contacts 2378, the relay R2375 opens another point in the path for short-circuiting the lower winding of the cut-off relay R2390 in series with the resistor 2396. At its contacts 2379, the relay R2375 interrupts the locking circuit for the relay R2350. The relay R2350 now restores and closes its contacts 2353 to reprepare the operating circuit for the relay R2360. At its contacts 2354, the relay R2350 disconnects the E. C. conductor C2334 from ground. At its contacts 2355, the relay R2350 opens another point in its own locking circuit. At its contacts 2352, the relay R2350 opens a point in the operating circuit for the relay R2375. At its contacts 2351, the relay R2350 connects the test conductor C2333 to ground through the contacts 2393, thereby to guard the trunk circuit 25 against seizure through the toll selectors until such time as this circuit is released at the switchboard 11.

When the resistor 2396 and the lower winding of the cut-off relay R2390 are included in the circuit for energizing the lower winding of the supervisory relay R2520, this supervisory relay is insufficiently energized to remain operated. In releasing, it closes its contacts 2521 to energize the rear supervisory lamp 2603. The steady illumination of this lamp serves to inform the operator attending the No. 1 position of the switchboard 11 that the calling end of the connection has been released. Upon receiving his disconnect signal, the operator at the first position of the switchboard 11 may release the link 15 by operating the link release key 2558. Incident to the release of the answer switch 16, the test conductor 25c is disconnected from ground to effect the deenergization and release of the cut-off relay R2390. Upon restoring, this relay closes its contacts 2391 to again bridge the terminating impedance 2397, 2398 across the talking conductors 25a and 25b of the trunk 25. At its contacts 2392 and 2393, the relay R2390 disconnects the test conductor C2333 from ground, connects this conductor to the negative terminal of the exchange battery, and reprepares the operating

circuit for the seizure relay R2370. At its contacts 2394, the relay R2390 opens another point in the path for connecting the E. C. conductor C2334 to ground in the trunk circuit 25. At its contacts 2395, the relay R2390 opens another point in its own locking circuit. Following the release of this relay the trunk circuit 25 is fully restored to normal.

In the event the connection is released at the switchboard 11 before the operator handling the call in the toll office No. 1 disconnects, the trunk circuit 25 is held through the operated switch train comprising the trunk circuit 26, the link 35 and the selector 32. In this case, the cut-off relay R2390 is deenergized and restores in response to the release of the link 15 occupied with the call. Upon restoring, the relay R2390 opens its contacts 2394 to deenergize the supervisory relay R540. The latter relay, upon restoring, transmits an on-hook supervisory signal to the operator handling the call in the distant toll office No. 1. Thereafter and when the trunk circuit 26, the link 35 and the selector 32 are all released under the control of the operator in the toll office No. 1, the relay R2365 is deenergized and restores and the test conductor C2333 is disconnected from ground to deenergize the relay R2375. The two relays R2365 and R2375, upon restoring, deenergize the relay R2350. Following the release of the last-mentioned relay the trunk circuit 25 is fully restored to normal and is marked as idle in the bank contacts of the selectors to which it is accessible.

CALL FROM THE SWITCHBOARD 11 TO THE TOLL OFFICE NO. 2

Calls may be routed to the toll office No. 2 from the toll operator switchboard 11 in the central office 10 either through the delayed call selectors associated with this switchboard or through the call switches individual to the different positions of the switchboard. To consider a call of this character it may be assumed that the trunk circuit 27 is seized through the outlet contacts of the call switch 17, in the extension of a connection from the No. 1 position of the switchboard 11 to the toll office No. 1. In this regard it will be understood from the preceding explanation that incident to the switch-through operation of the call switch 17, the talking conductors C1148 and C1146 of the trunk 27f are connected through the contacts 2651 and 2652 of the operated start send relay R2650 to the pulsing leads C2661 and C2662 and that the last-mentioned leads are connected together through the sender control circuit 20 and the contacts 4306 of the relay R4300 in the impulse sender 21A. Also incident to the switch-through operation of the call switch 17, the E. C. conductor C1280 of the trunk 27f is connected through the contacts 2653 to the E. C. lead C2663 extending to the sender control circuit 20, thereby to prepare a circuit over which the supervisory relay R3530 of the sender control circuit may be controlled. Also incident to the switch-through operation of the call switch 17, the test conductor C1279 of the trunk 27f is connected to ground to complete the previously traced operating circuit for the seizure relay R1140.

When thus energized, the relay R1140 operates to cause the operation of the three relays R1130, R1030 and R920 in the exact manner explained above with reference to the extension of a connection to the toll office No. 2 from the toll office No. 1. In the present case, the switching relay

R1130, in closing its contacts 1132' and 1134', energizes the serially related windings of the differential relay R1120 and the loop pulse relay R1110 in a balanced loop circuit which includes the contacts 4332 of the pulse generating relay in the impulse sender 21A as shunted by the contacts 4306 of the digit space relay R4300. More specifically, this circuit as initially completed between the impulse sender 21A and the trunk circuit 27 extends from ground by way of the upper winding of R1110, the upper winding of R1120, the contacts 1132' and 932, the winding 814, the contacts 1135 and 1274, C1146, one side of the talking circuit through the call switch 17, the contacts 2652, C2662, the contacts 3401, 3701, 3711 and 3721, the pulsing lead E1, the contacts 4332 and 4306 in parallel, the pulsing lead F1, the contacts 3722, 3712, 3702, 3613 and 3402, C2661, the contacts 2651, the other side of the talking circuit through the call switch 17, C1148, the contacts 1272 and 1133, the winding 813, the contacts 934 and 1134', the lower winding of R1120, the contacts 936 and 1021, and the lower winding of R1110 to battery. It will be noted that both sides of this loop circuit are free of any connections to ground and that, accordingly, the relay R1120 is differentially energized therein and does not operate.

When energized in the above-traced loop circuit, the loop pulse relay R1110 closes its contacts 1111 to short-circuit the control relay R1030, whereby the two relays R1030 and R920 are sequentially released. At its contacts 1112 and 1113, the relay R1110 substitutes negative battery potential for ground potential upon the signal lead C1025 and the two conductors of the trunk 6, whereby the trunk circuit terminating this trunk in the distant toll office No. 2 and a toll pre-selector accessible to the indicated trunk circuit are seized and conditioned to respond to the continued operation of the impulse sender 21A. In this regard it is noted that the switch-through operation of the call switch 17, the seizure of the trunk circuit 27 in the manner just explained, the seizure of the trunk circuit terminating the trunk 6 in the distant toll office No. 2, and the seizure of the incoming toll selector associated with this trunk circuit, are all effected during the inter-digit pause separating the first and second digits transmitted by the impulse sender 21A.

During the continued operation of the impulse sender 21A the loop pulse relay R1110 functions to repeat the switch directing impulses to the automatic switching equipment provided in the distant toll office No. 2. In this regard it will be noted from a consideration of the above-traced loop circuit that each time the contacts 4332 of the pulse generating relay R4330 are opened during an impulse sending period, the loop pulse relay R1110 is deenergized and restores to reconnect the signal lead C1025 to ground through its contacts 1113. Conversely, each time the pulsing contacts 4332 of the pulse generating relay R4330 are closed at the end of the open-circuit period of an impulse, the loop pulse relay R1110 reoperates to substitute negative battery potential for ground potential upon the signal lead C1025. The alternate pulses of ground and negative battery potential as applied to the two conductors of the trunk 6 over the signal lead C1025 are translated into standard switch directing pulses by the signal relay of the trunk circuit terminating the trunk 6 in the distant toll office. These translated impulses are utilized to direct the call to the desired destination, whether it be a substation accessible to the toll switching equipment of the toll office

No. 2 or the toll switchboard provided in this office. The control relay R1030 also follows the operation of the loop pulsing relay R1110 during each series of impulses transmitted by the register sender 21. Each time the relay R1030 operates it closes its contacts 1031 to complete a circuit through the contacts 932' and 1163 for energizing the slow-acting relay R920. Accordingly, the relay R920 is operated at the beginning of each digit and remains operated until shortly after the digit is ended. This relay, upon operating, closes its contacts 921' to complete an obvious path for shunting the repeating coil winding 813, whereby the resistance of the loop circuit over which impulses are transmitted to the loop pulse relay R1110 is decreased. At its contacts 921, the relay R920 also opens a point in the operating circuit for the supervisory relay R810. The remaining circuit switching operations performed by the digit relay R920 are without effect.

From the preceding explanation pertaining to the operation of the register sender 21 and the sender control circuit 20, it will be recalled that when all digits have been registered in the digit registers 21B, the disconnect key of the key set 22 is operated to effect the operation of the sender disconnect relay R3630, followed by the release of the sender connect relay R3700 and the sender supervisory relay R3640. Thereafter, and when all registered digits have been transmitted by the impulse sender 21A and the hold relay R4380 restores, the high resistance upper winding of the start relay R4350 is excluded from the circuit for energizing this relay in series with the release relay R3610. When thus fully energized, the relay R3610 opens its contacts 3613 to interrupt the loop circuit extending to the trunk circuit 27, and closes its contacts 3612 to connect the negative side of this loop circuit to ground through the winding of the relay R3600. Thus the release relay R3610, upon operating, unbalances the established loop circuit to deenergize the respective upper windings of the two relays R1110 and R1120. In operating, the release relay R3610 also opens its contacts 3614 to deenergize the hold relay R3620.

The relay R3600 operates when energized over the negative side of the loop circuit in the manner just explained. At its contacts 3601, this relay opens a point in the operating circuits for the relays R2620 and R3320. At its contacts 3602, the relay R3600 closes an obvious circuit for energizing the relay R3510. At its contacts 3604, the relay R3600 opens a point in the operating circuits for the relays R3440 and R3520. At its contacts 3603, the relay R3600 prepares the locking circuit for the hold relay R3620. The relay R3510, upon operating, closes its contacts 3513 to initiate vibration of its weighted armature 3512 and thus prepare the operating circuit for the slow-to-operate relay R3500. At its contacts 3511, the relay R3510 prepares a locking circuit for itself. At its contacts 3514, the relay R3510 prepares the operating circuit for the relay R3440.

When its lower winding is alone energized, the differential relay R1120 operates and closes its contacts 1121 to energize the differential slave relay R1070. The latter relay, upon operating, closes its contacts 1071 to prepare a locking circuit for itself; opens its contacts 1072 to disconnect the E. C. conductor C1280 from ground in the trunk circuit 27; closes its contacts 1074 to complete a more direct path for impressing negative battery potential upon the signal lead C1025; and opens its contacts 1075 to interrupt the path

through the pulsing contacts 1112 over which negative battery potential is impressed upon the signal lead C1205 during the impulsive period. At its contacts 1073, the relay R1070 also completes a circuit for energizing the control relays R950 and R960 in series with the supervisory relay R3530 of the sender control circuit 20. This circuit may be traced as extending from ground by way of the contacts 3621, the winding of R3530, the contacts 3404, C2663, the contacts 2653, the E. C. control path through the call switch 17, C1280, the contacts 1142 and 1073, and the series-connected windings of the two relays R960 and R950 to battery. Due to the relatively high resistance of the windings of the two relays R3530 and R960, only these two relays operate when this circuit is completed. More specifically, the relay R950 is marginally not to operate when energized in the above-traced circuit.

The relay R3530, upon operating, closes its contacts 3533 to initiate vibration of its weighted armature 3532. At its contacts 3531, the relay R3530 opens a point in one of the available circuits for energizing the relay R3510. At its contacts 3534, the relay R3530 completes the prepared locking circuit for the slow-to-release hold relay R3620, this circuit extending from ground by way of the contacts 3534, 3603 and 3502, and the winding of R3620 to battery. Thus the relay R3530, in operating, prevents the hold relay R3620 from releasing to initiate the cut-through operation of the link 15, the release of the register sender 21, and the release of the sender control circuit 20 in the manner explained above, until such time as the trunk circuit 27 has shifted to a setting wherein the loop extending from this trunk back to the link 15 is dried in the manner explained below. In this case, the vibration of the weighted armature 3532, as initiated in response to energization of the supervisory relay R3530, prevents the slow-to-operate relay R3540 from operating.

The control relay R960, upon operating in the trunk circuit 27, closes its contacts 961 to prepare the operating circuit for the switching relay R930 and, at its contacts 962, completes the operating circuit for the control relay R970. The relay R970 now operates and closes its contacts 971 to complete the prepared locking circuit for the differential slave relay R1070. At its contacts 972, the relay R970 opens a point in the path for conductively connecting the inner terminals of the repeating coil windings 813 and 814. At its contacts 973, the relay R970 completes the prepared operating circuit for the switching relay R930. At its contacts 974, the relay R970 prepares the previously traced locking circuit for the supervisory relay R1040.

The switching relay R930, upon operating, opens its contacts 932 and 934 further to interrupt the loop circuit as initially established between the trunk circuit 27 and the impulse sender 21A. Thus the previously described circuits for energizing the loop pulse relay R1110, the differential relay R1120 and the relay R3600 are broken. At its contacts 931 and 933, the relay R930 prepares the path for conductively connecting the inner terminals of the repeating coil windings 813 and 814. At its contacts 933, the relay R930 also prepares the operating circuit for the rering relay R980. At its contacts 935, the relay R930 closes the prepared locking circuit for the loop pulsing relay R1110, this circuit extending from ground by way of the current limiting resistor 963, the contacts 944, 935 and 1021, and the lower winding of R1110 to battery. After completing this circuit

the relay R930 opens its contacts 936 to interrupt both branches of the previously traced circuit for energizing the respective lower windings of the two relays R1110 and R1120 in series. At its contacts 937, the relay R930 opens a point in the prepared path through the resistor 965 for impressing negative battery potential upon the E. C. conductor C1280. At its contacts 938, the relay R930 prepares a path for connecting the E. C. conductor C1280 to ground. At its contacts 939, the relay R930 opens a point in the available local circuit for energizing the two control relays R950 and R960 in series. At its contacts 931', the relay R930 locks to ground through the contacts 1143. At its contacts 932', the relay R930 opens a point in the previously traced operating circuit for the digit relay R920.

When deenergized in the manner explained above, the differential relay R1120 opens its contacts 1121 to interrupt the operating circuit for the differential slave relay R1070. The latter relay is, however, held energized over this locking circuit until such time as the control relay R960 is released under the control of the sender control circuit 20.

As indicated in the above explanation, when the switching relay R930 opens its contacts 934, the circuit over which the relay R3600 is energized in series with the lower windings of the two relays R1110 and R1120, is broken. In releasing, the relay R3600 opens its contacts 3602 to de-energize the relay R3510. At its contacts 3601, the relay R3600 prepares the previously traced operating circuits for the relays R2620 and R3320. At its contacts 3603, the relay R3600 opens the above-traced locking circuit for the slow-to-release hold relay R3620. At its contacts 3604, the relay R3600 completes the prepared operating circuits for the relays R3520 and R3440.

The relay R3520, upon operating, locks to ground through its preliminary make contacts 3524 and the contacts 3501 and 3408, and then opens its operating circuit at the contacts 3525. At its contacts 3523, the relay R3520 connects the E. C. 1 lead to ground. At its contacts 3521, the relay R3520 closes a locking circuit for the relay R3510. At its contacts 3522, the relay R3520 prepares another locking circuit for the relay R3510. The relay R3440, in operating, locks to ground through the contacts 3443; closes ground to the sender disconnect lead through its contacts 3444; closes its contacts 3445 to complete a locking circuit for the release relay R3610; closes its contacts 3442 to complete an obvious multiple path for impressing ground potential upon the E. C. 1 lead; and opens its contacts 3441 to interrupt the operating circuit for the relay R3540.

The hold relay R3620, upon restoring in response to the release of the relay R3600, opens its contacts 3621 to interrupt the above-traced circuit for energizing the supervisory relay R3530 in series with the two control relays R950 and R960, whereby the two relays R3530 and R960 are caused to restore. At its contacts 3622, the relay R3620 deenergizes the sender disconnect relay R3630. The latter relay, upon restoring, effects the release of the register sender 21 and the cut-through operation of the link 15 in the exact manner previously explained. From this explanation it will be recalled that incident to the cut-through operation of the link 15, the operating circuit for the sender start relay R3420 is opened in the position circuit 18. Upon restoring, the relay R3630 also opens its contacts 3639 to de-energize the release relay R3610. The latter re-

70 operation it will be recalled that incident to the cut-through operation of the link 15, the operating circuit for the sender start relay R3420 is opened in the position circuit 18. Upon restoring, the relay R3630 also opens its contacts 3639 to de-energize the release relay R3610. The latter re-

lay, in releasing, opens its contacts **3615** to de-energize the connect relay **R3400**. Upon restoring, the relay **R3400** opens its contacts **3408** to deenergize the relays **R3440** and **R3520**. The latter relay, in releasing, opens its contacts **3521** and **3522** to deenergize the relay **R3510**. Following the release of the last-mentioned relay, the sender control circuit **20** is fully restored to normal.

When the relay **R3600** restores to deenergize the control relay **R960**, the latter relay releases and opens its contacts **961** to interrupt the operating circuit for the switching relay **R930**. At its contacts **962**, the relay **R960** deenergizes the control relay **R970**. This control relay now restores and opens its contacts **971** to deenergize the differential slave relay **R1070**. The latter relay, upon restoring, opens its contacts **1073** to disconnect the E. C. conductor **C1280** from the negative terminal of the exchange battery, and closes its contacts **1072** to connect this conductor to ground through the contacts **912** and **948**. At its contacts **1074** and **1075**, the relay **R1070** also rearranges the path over which the signal lead **C1025** is connected to the negative terminal of the exchange battery through the resistor **1101**.

Incident to the switch-through operation of the link **15** in the manner pointed out above, the start send relay **R2650** is deenergized and restores to disconnect this link from the sender control circuit **20**. Also incident to the cut-through operation of this link, the cut-through relay **R2620** is operated to prepare a circuit including the E. C. control path extending to the trunk circuit **27** for energizing the front supervisory relay **R2600**. This circuit is completed in an obvious manner when the differential slave relay **R1070** closes its contacts **1072** to terminate the mentioned E. C. control path at ground through the contacts **912** and **948**. When thus energized, the front supervisory relay **R2600** closes its contacts **2601** to complete a circuit through the contacts **2532** for energizing the front supervisory lamp **2516**. Thus the operator attending the No. 1 position of the switchboard **11** is informed that the call has been extended to the desired destination.

When the call is answered at the called substation or at the toll switchboard in the distant toll office No. 2, the two conductors of the trunk **6** are connected to the negative terminal of the battery provided in this office. Thus the required circuits are established for effecting the operation of the signal relay **R820**. In operating, this relay closes its contacts **821** to complete a circuit through the contacts **1139** and **921** for energizing the supervisory relay **R910**. In operating, the relay **R910** closes its contacts **913** to prepare a circuit for energizing the switching relay **R930**. At its contacts **912**, the relay **R910** disconnects the E. C. conductor **C1280** from ground, thereby to interrupt the established circuit for energizing the front supervisory relay **R2600**. At its contacts **911**, the relay **R910** prepares paths through the contacts **937** and **938**, respectively, for impressing negative battery and ground potential upon the E. C. conductor **C1280**. When deenergized in response to the operation of the supervisory relay **R910**, the front supervisory relay **R2600** of the link **15** opens its contacts **2601** to deenergize the front supervisory lamp **2516**, whereby the operator attending the No. 1 position of the switchboard **11** is provided with a visual indication that the call has been answered. In this regard it will be noted that after the desired connection is fully established between the calling and called subscribers, the operator handling the call at the

switchboard **11** may release her position circuit **18** and rely upon the two lamps **2516** and **2603** to produce the supervisory signals required to keep her informed as to the condition of the connection. It will also be recalled that incident to the release of the position circuit **18** the start relay **R2530** is deenergized and closes its contacts **2534** to complete a circuit, including the E. C. control path extending to the trunk circuit **26**, over which the front supervisory lamp **2516** may be directly controlled by the supervisory relay **R910**. If, with the connection thus established, a flashing recall signal is transmitted to the trunk circuit terminating the trunk **6** in the toll office No. 2, either from the answering substation served by this office or from the toll switchboard provided in this office, the supervisory relays of the indicated trunk circuit function intermittently to disconnect the two conductors of the trunk **6** from the negative terminal of the battery provided in this toll office. The signal relay **R820**, in following the splashes of negative battery potential applied to the two conductors of the trunk **6** transmits a corresponding number of open-circuit pulses to the supervisory relay **R910**. This supervisory relay, in following the impulses generated at the contacts **821** by the signal relay **R820**, alternately closes and opens its contacts **912**, thereby intermittently to energize the front supervisory lamp **2516**. Thus a flashing signal is produced by this lamp, which indicates to the operator attending the No. 1 position of the switchboard **11** that she is being recalled from the called substation or toll switchboard in the toll office No. 2. From the above explanation it will be understood that when the called subscriber or the operator handling the call in the toll office No. 2 disconnects, the signal relay **R820** is released and remains in its restored position. This relay, in restoring, opens its contacts **821** to deenergize the supervisory relay **R910**. The latter relay, in restoring, closes its contacts **912** to energize the front supervisory lamp **2516**. The steady illumination of this lamp serves to inform the operator attending the No. 1 position of the switchboard that the connection has been released at the distant end thereof in the toll office No. 2. If the call is extended to the toll switchboard in the toll office No. 2, and the operator handling the call at the No. 1 position of the switchboard **11** desires to resignal the operator handling the call in the toll office No. 2 before the connection is released in this toll office, she may do so by reconnecting her position circuit **18** to the link **15** and then actuating the ring front key **4050** for a short interval. When this key is operated to its off-normal position, ringing current is transmitted over the negative side of the talking circuit to the trunk circuit **27**, in a manner which will be clearly apparent from the preceding explanation. More specifically, each time this key is operated, the talking conductor **C1148** of the trunk **27** is connected to the ungrounded terminal of the ringing current generator to energize the rering relay in a circuit which includes the contacts **1272** and **1133**, the repeating coil winding **813**, the contacts **933** and **942**, and the condenser **964**. When energized by ringing current traversing this circuit, the relay **R980** opens its contacts **981** to deenergize the normally operated rering relay **R1010**. The latter relay releases after an interval and closes its contacts **1011** to shunt the contacts **1021** as included in the holding circuit for the loop pulse relay **R1110**. At its contacts **1012**, the relay **R1010** energizes the slow-to-

release rering relay R1020. The latter relay, upon operating, opens its contacts 1021 to interrupt the path shunting the contacts 1011.

When the ring front key 4050 is released to terminate the ringing interval, the relay R980 restores and closes its contacts 981 to again energize the relay R1010. The latter relay, upon operating, opens its contacts 1011 to deenergize the loop pulse relay R1110. At its contacts 1012, the relay R1010 deenergizes the relay R1020.

The loop pulse relay R1110, upon restoring, opens its contacts 1111 to interrupt the path short-circuiting the control relay R1010. When this path is broken the control relay R1030 is again energized over a circuit which extends to ground through the contacts 1141; but the re-operation thereof is without effect. At its contacts 1112 and 1113, the relay R1110 substitutes ground potential for negative battery potential on the signal lead C1025 and the conductors of the trunk 6, thereby to transmit an on-hook supervisory signal to the operator handling the call in the distant toll office No. 2.

Shortly following the release of the loop pulse relay R1110, the slow-to-release rering relay R1020 restores and recloses its contacts 1021 to again energize the loop pulse relay R1110. In reoperating, the loop pulse relay R1110 closes its contacts 1111 to short-circuit the control relay R1010 and, at its contacts 1112 and 1113, substitutes negative battery potential for ground potential on the signal lead C1025 and the conductors of the trunk 6, thereby to transmit an off-hook supervisory signal to the operator handling the call in the toll office No. 2. From the above explanation it will be understood that the duration of the on-hook supervisory signal transmitted to the distant operator is measured by the release period of the rering relay R1020, which period is of the order of 50-120 milliseconds. It will also be understood from the preceding explanation that the described cycle of the five relays R980, R1010, R1020, R1110 and R1030 is repeated each time a splash of ringing current is transmitted from the position circuit 18 over the talking conductor C1148 of the trunk 27.

The release of the link 15 and the trunk circuit 27 occupied with the call in the central office 10 is entirely under the control of the originating operator at the No. 1 position of the switchboard 11. The manner in which the link 15 is released in response to operation of the link release key 2556 is exactly the same as explained above. Incident to the release of this link, the test conductor C1279 is disconnected from ground in the link to effect the deenergization and release of the seizure relay R1140. This relay, in restoring, opens its contacts 1141 to deenergize the switching relay R1130 and to interrupt the circuit for energizing the control relay R1030. At its contacts 1143, the relay R1140 deenergizes the switching relay R930. The relay R1130, upon restoring, opens its contacts 1139 to deenergize the supervisory relay R910, if operated. The switching relay R930, upon restoring, opens its contacts 935 to deenergize the loop pulse relay R1110. Following the release of the six relays R1140, R1130, R1110, R1030, R930 and R910, the trunk circuit 27 is fully restored to normal. In this regard it will be noted that when the test conductor C1279 is disconnected from ground in the link 15, negative battery potential is impressed upon this conductor through the winding of the seizure relay R1140, whereby the trunk circuit 27 is marked as idle in the toll selectors to

which it is accessible. It will also be noted that the loop pulse relay R1110, upon restoring, opens its contacts 1112 and closes its contacts 1113, whereby ground potential is substituted for negative

5 battery potential upon the signal lead C1025 and the two conductors of the trunk 6. On this point it is noted that normally the originating operator at the No. 1 position of the switchboard 11 will not release the connection through the 10 link 15 and the trunk circuit 27 until a disconnect supervisory signal is produced by the front supervisory lamp 2516, which, of course, means that the supervisory relay R910 is released in the 15 trunk circuit 27 at the time the release of this trunk circuit is initiated.

As indicated above, the trunk circuit 27 may also be seized from the No. 1 position of the switchboard 11, for example, through the answer switch 16 and the delayed call selector 41, for 20 example, by appropriate operation of the keys provided at this position of the switchboard. The manner in which the seizure of the trunk circuit 27 is effected through the switches 16 and 41 will be clearly apparent from the preceding 25 explanation with reference to the mode of handling delayed calls at the first position of the switchboard. It is noted, however, that after the trunk circuit 27 is seized by the delayed call selector 41 the conductors 41a, 41b, 41c and 41e 30 are connected respectively to the conductors C1148, C1146, C1279 and C1280. Accordingly, it will be understood that the loop circuit as established between the trunk circuit 26 and the impulse sender 21A includes the wipers 2401 and 35 2402 of the answer switch 16 and the rear talking leads C2573 and C2575 of the position circuit 18. It is also noted that the E. C. control path as established between the sender control circuit 20 and the trunk circuit 27 includes the wiper 2408, 40 the contacts 2441', the normal post springs 2420, the contacts 2531', C2569, the contacts 3341', C2663, and the contacts 3404. With the loop circuit and the described E. C. control path established between the sender control circuit 20 and the trunk circuit 27, the various supervisory and 45 control signals required to effect the extension of the connection may be carried out in a manner which will be readily apparent from the preceding explanation.

50

Delay in dialing.

If, in extending the above-described call through the toll switching equipment provided in the toll office No. 2 to the desired destination, a 55 switching stage is reached at which a time interval exceeding the normal inter-digit pause between two successive digits is required in order to condition the succeeding switching equipment to receive the next digit, the control equipment at 60 the last seized switching stage functions to transmit a signal to the trunk circuit terminating the trunk 6 in the toll office No. 2 which results in the application of negative battery potential to the two conductors of the trunk 6. This potential 65 as applied to the two sides of the trunk 6 constitutes a stop-in-dial or delay send signal and may be received during the inter-digit pause separating any two of the digits transmitted to the trunk 27 from the register sender 21. In this 70 regard it will be noted that when the two sides of the trunk 6 are connected to the negative terminal of the battery provided in the toll office No. 2, the signal relay R820 is operated to complete the above-traced operating circuit for the 75 supervisory relay R910. Under the circumstances

now being considered, the switching relay R830 has not operated in the trunk circuit 27. Accordingly, the supervisory relay R910, in operating, connects the E. C. conductor of the trunk 27 to the negative terminal of the exchange battery over a patch which includes the contacts 1072, 911 and 937, and the resistor 965. When this patch is completed, the supervisory relay R3530 is energized in the sender control circuit 20. In operating, the relay R3530 initiates vibration of its weighted armature 3532, opens its contacts 3531, and closes its contacts 3534 to energize the relay R3520 in a circuit which includes the contacts 3604 and 3525. The relay R3520 now operates and locks to ground through its preliminary make contacts 3524 and the contacts 3501 and 3408. After completing this locking circuit, the relay R3520 interrupts its operating circuit at the contacts 3525. At its contacts 3522, the relay R3520 prepares one of the circuits for energizing the relay R3510. At its contacts 3521, the relay R3520 prepares a locking circuit for the relay R3510. At its contacts 3523, the relay R3520 completes a circuit for energizing the stop send relay R4310 of the impulse sender 21A, this circuit extending from ground by way of the contacts 3523, the contacts 3636 or 3708, the contacts 3717 and 3721, the E. C. 1 lead, the contacts 4294, and the winding of R4310 to battery. The stop send relay R4310, upon operating, arrests the operation of the impulse sender 21A in the exact manner previously explained.

When the stop-in-dial signal is terminated in the trunk circuit terminating the trunk 6 in the toll office No. 2, i. e., when the two conductors of the trunk 6 are disconnected from the negative terminal of the battery provided in this office, the three relays R820, R910 and R3530 are released in the order named. The relay R3530, upon restoring, opens its contacts 3533 to prevent the operation of the relay R3540; opens its contacts 3534 to interrupt the operating circuit for the relay R3520; and closes its contacts 3531 to complete the circuit through the contacts 3522 for energizing the relay R3510. The relay R3510, in operating, locks to ground through the contacts 3511 and 3521. At its contacts 3514, the relay R3510 prepares the operating circuit for the relay R3440. In closing its contacts 3513, the relay R3510 also initiates vibration of the weighted armature 3512. So long as this armature continues to vibrate, the circuit through the contacts 3513 for energizing the relay R3500 is only intermittently completed and this relay, due to its slow-to-operate characteristic, does not operate. After a predetermined time interval, vibration of the armature 3512 is arrested, permitting the contacts 3513 to settle into resting engagement. When continuously energized through the contacts 3513, the relay R3500 operates after an interval and opens its contacts 3501 to deenergize the relay R3520. At its contacts 3502, the relay R3500 opens a point in the above-traced locking circuit for the hold relay R3620. The relay R3520 now restores and opens its contacts 3521 and 3522 to deenergize the relay R3510. At its contacts 3523, the relay R3520 deenergizes the stop send relay R4310 in the impulse sender 21A. At its contacts 3524 and 3525, the relay R3520 opens another point in its own locking circuit and reprepares its operating circuit. The relay R3510, in releasing, opens its contacts 3513 to deenergize the relay R3500. At its contacts 3514, the relay R3510 opens the prepared operating circuit for the re-

lay R3440. At its contacts 3511, the relay R3510 opens another point in its own locking circuit. The relay R3500, upon restoring, closes its contacts 3501 to reprepare the locking circuit for the relay R3520 and, at its contacts 3502, reprepares the locking circuit for the hold relay R3620.

When the stop send relay R4310 of the impulse sender 21A is deenergized, it releases to reinitate the step-by-step operation of the counting network provided in the impulse sender, whereby these relays are operated to measure the normal inter-digit spacing interval. At the end of this interval, the transmission of the stored digits as registered in the digit registers 21B is started. From the foregoing explanation it will be understood that the relays R3530, R3520, R3510 and R3500 not only cooperate to repeat the received stop-in-dial or delay send signal to the impulse sender 21A, but also function to measure a predetermined time interval between the termination of this signal and the restarting of the impulse sender 21A. This time interval is primarily determined by the operating time of the relay R3510, i. e., the time required for the armature 3512 to stop vibrating. The purpose of introducing this delay at the end of a received stop-in-dial signal is to insure that the seized switches in the distant toll office No. 2 are fully conditioned to receive impulses before restarting the operation of the sender 21A.

Blocked switching stage in the district toll office

If the above-described call as extended to the toll office No. 2 is routed to a blocked switching stage, i. e., a stage at which an all-trunks-busy condition is encountered, for example, one of two different control signals will be returned over the trunk 6 to the trunk circuit 27, depending upon the wiring of the toll switching equipment as provided in this office. In this regard it will apparent that if the toll selectors as provided in the toll office No. 2 are of the same type as the selectors 37, 32 and 34, for example, a flash busy signal will be transmitted over the trunk 6 to the trunk circuit 27 when the all-busy condition is encountered. This flash busy signal is transmitted over the trunk 6 by intermittently connecting the conductors of this trunk to the negative terminal of the battery provided in the toll office No. 2 at a rate of 60 or 120 times per minute. On the other hand, if the toll selectors as provided in the toll office No. 2 are of conventional design, a steady off-hook supervisory signal is transmitted over the trunk 6 to the trunk circuit 27 when an all-trunk-busy condition is encountered in extending a connection therethrough. In the latter case, the two conductors of the trunk 6 are connected to the negative terminal of the battery provided in the toll office No. 2 and the connection is not interrupted. In either case, the signal relay R820 is operated when the conductors of the trunk 6 are connected to the negative terminal of the battery provided in the toll office No. 2 and remains operated until this connection is broken.

Assuming first that the signal relay is operated in response to the transmission of a steady off-hook supervisory signal over the trunk 6, this relay closes its contacts 821 to energize the supervisory relay R910. The latter relay, upon operating, closes its contacts 911 to energize the supervisory relay R3530 of the sender control circuit 20 in series with the resistor 965. The supervisory relay R3530, upon operating, effects the operation of the relays R3520 and R4310 in

the manner explained above, whereby the operation of the impulse sender 21A is arrested. In operating, the relay R3530 also initiates the vibration of its weighted armature 3532. After a predetermined time interval which exceeds the normal interval during which a stop-in-dial signal may persist in the manner explained above, vibration of the weighted armature 3532 is arrested, permitting the contacts 3533 to settle into resting engagement wherein a circuit through the contacts 3441 is completed for energizing the slow-to-operate relay R3540. When thus continuously energized, the relay R3540 operates after an interval and opens its contacts 3541 to interrupt the previously traced circuit for energizing the sender pilot lamp 4125. At its contacts 3542, the relay R3540 completes a circuit including the 120 I. P. M. lead C2637 for intermittently energizing the sender pilot lamp 4125. At its contacts 3543, the relay R3540 closes the prepared operating circuit for the blocked sender relay R2610 of the link 15 occupied with the call. In the event the connection has been extended to the distant toll office No. 2 through the front end of this link, the operating circuit for the blocked sender relay R2610 may be traced as extending from ground by way of the contacts 3543 and 3406, C2666, the contacts 2656, and the winding of R2610 to battery. On the other hand, if the connection has been extended to the toll office No. 2 through the rear end of the link 15, i. e., through the answer switch 16 and the delayed call selector 47, for example, the relay R2650 is not operated in the link 15 but the dial rear relays R2340 and R3350 are operated in the position circuit 18. In this case the operating circuit for the blocked sender relay R2610 may be traced as extending from ground by way of the contacts 3543 and 3406, C2666, the contacts 3351, C2578, the contacts 2588, and the winding of R2610 to battery. When energized over either of these circuits, the relay R2610 closes its contacts 2611 to complete an obvious circuit for energizing the busy lamp 2604 in accordance with the ground pulses transmitted over the 120 I. P. M. lead C2637. Upon observing the flashing of the lamps 2604 and 4125, the operator attending the No. 1 position of the switchboard is informed that a blocked switching stage has been encountered in the extension of the connection. Upon receiving this information she may release the connection as extended, either through the front or the rear end of the link 15 by momentarily depressing the error key of the key set 22 to effect the operation of the error relay R3410. This relay, in operating, initiates the release of the register sender 21 and the sender control circuit 20 in the exact manner previously explained. In the present case, the supervisory relay R3530 is deenergized and restores in response to the release of the hold relay R3620. In releasing, the relay R3530 opens its contacts 3533 to deenergize the relay R3540, and closes its contacts 3531 to energize the relay R3510. The relay R3540, upon restoring, opens its contacts 3543 to interrupt the completed operating circuit for the blocked sender relay R2610. When the two relays R3430 and R3400 are thereafter deenergized, the locking circuit for the relay R3520 is opened at the contacts 3408. In releasing, the relay R3520 opens its contacts 3521 and 3522 to deenergize the relay R3510. Thus the four relays R3530, R3540, R3520 and R3510, which are operated when blocked switching stage is encountered in the 75

distant toll office No. 2, are all deenergized in response to operation of the error relay R3410. The blocked sender relay R2610, upon restoring, opens its contacts 2611 to interrupt the circuit for transmitting ground pulses from the 120 I. P. M. lead C2637 to the busy lamp 2604. At its contacts 2612, the relay R2610 recomplices the circuit for energizing this lamp in accordance with the ground pulses transmitted over the 60 I. P. M. lead C2638. The change in the rate of flashing of the busy lamp 2604, accompanied by the deenergization of the sender pilot lamp 4125, serves to inform the operator handling the call at the No. 1 position of the switchboard 11 that the sender control circuit 20 and the register sender 21 have been released. Upon receiving this information the operator may release either the front or the rear end of the link 15 through which the call is extended to the distant toll office No. 2, thereby to effect the release of the trunk circuit 27 and the operated switches in the distant toll office in a manner which will be clearly apparent from the above explanation. If a flash busy control signal is transmitted over the trunk 6 to the signal relay R820 when the all-trunks-busy condition is encountered in the distant toll office No. 2, this relay in intermittently operating and releasing functions to repeat the signal to the supervisory relay R910. The relay R910, in following the signal, alternately opens and closes its contacts 911, thereby to repeat the signal to the supervisory relay R3530. This relay, upon operating at the beginning of the first battery pulse transmitted over the E. C. control path by the supervisory relay R910, effects the operation of the relay R3520 in the manner explained above. The relay R3520, in operating, prepares the operating and locking circuits for the relay R3510, closes the operating circuit 40 for the stop send relay R4310, locks to ground through the contacts 3408, and opens its operating circuit, all in the manner explained above. At the end of the first negative battery pulse transmitted over the E. C. control path by the supervisory relay R910, the supervisory relay R3530 restores and closes its contacts 3531 to energize the relay R3510. The latter relay, in operating, locks to ground through the contacts 3511 and 3521, closes its contacts 3514 to prepare the operating circuit for the relay R3440, and initiates the vibration of its weighted armature 3512.

At the beginning of the second battery pulse transmitted over the E. C. control path by the supervisory relay R910, the relay R3530 reoperates and closes its contacts 3534 to complete the prepared operating circuit for the relay R3440. This circuit extends from ground by way of the contacts 3534, 3604 and 3514, and the winding of R3440 to battery. When thus energized, the relay R3440 locks to ground through the contacts 3443 and 3408. At its contacts 3442, the relay R3440 completes an obvious shunt across the contacts 3523, thereby to provide a holding circuit for the stop send relay R4310. At its contacts 3441, the relay R3440 opens a point in the operating circuit for the relay R3540. In this regard it is noted that, due to the intermittent operation of the relay R3530 and the resulting continued vibration of the weighted armature 3532, the relay R3540 does not operate in response to the intermittent operation of the supervisory relay R3530.

In operating, the relay R3440 also closes its contacts 3444 to complete a circuit including the disconnect lead C3644 and the contacts 3707 for

energizing the sender disconnect relay R3630, providing this relay has not previously been operated under the control of the disconnect key in the key set 22. At its contacts 3445, the relay R3440 prepares an alternative circuit for energizing the release relay R3610. Following the operation of the relay R3440 the continued intermittent operation of the supervisory relay R3530 is without effect.

If the sender disconnect relay R3630 is operated in response to the operation of the relay R3440, it performs the previously described switching operations. In this case, however, the relay R3630, upon closing its contacts 3639, energizes the release relay R3610 over a branch circuit which includes the contacts 3445 and the resistor 3446. When this branch circuit is completed, either at the contacts 3639 or the contacts 3445, the relay R3610 operates and closes its contacts 3611 to prepare the previously traced circuits for energizing the relays R2620 and R3320. At its contacts 3612, the relay R3610 connects the negative side of the loop circuit extending to the trunk circuit 27 to ground through the winding of the relay R3600, whereby the latter relay is energized in series with the respective lower windings of the two relays R1110 and R1120, and the respective upper windings of the two last-mentioned relays are deenergized. After completing this series energizing circuit, the relay R3610 opens its contacts 3613 to interrupt the loop circuit as initially completed between the impulse sender 21A and the trunk circuit 27. At its contacts 3614, the relay R3610 opens the operating circuit for the hold relay R3620. At its contacts 3615, the relay R3610 completes a multiple holding circuit for the connect relay R3400.

When energized in series with the series-connected lower windings of the two relays R1110 and R1120, the relay R3600 closes its contacts 3602 to complete an obvious multiple holding circuit for the relay R3510. At its contacts 3601, the relay R3600 opens a point in the previously traced operating circuits for the cut-through relay R2620 and the cut-in relay R3320. At its contacts 3603, the relay R3600 completes a circuit including the contacts 3534 and the contacts 3502 for transmitting ground pulses through the hold relay R3620 during continued operation of the supervisory relay R3530. At its contacts 3604, the relay R3600 opens a point in the previously traced operating circuits for the two relays R3520 and R3440.

When its upper winding is deenergized in response to operation of the release relay R3610 in the manner just explained, the relay R1120 operates and closes its contacts 1121 to cause the operation of the differential slave relay R1070. The latter relay, upon operating, opens its contacts 1072 to interrupt the E. C. control path over which negative battery pulses are being transmitted to the supervisory relay R3530 under the control of the relay R910. At its contacts 1073, the relay R1070 completes the previously traced circuit for energizing the supervisory relay R3530 in series with the two control relays R950 and R960. When thus continuously energized, the supervisory relay R3530 remains in its operated position and holds its contacts 3534 closed to maintain the previously traced holding circuit for the slow-to-release hold relay R3620.

The control relay R960, upon operating, closes its contacts 961 and 962 to effect the sequential operation of the control relay R970 and the switching relay R930 in the manner previously pointed out. The switching relay R930, upon op-

erating, locks to ground through its contacts 931, closes its contacts 935 to complete the previously traced locking circuit for the loop pulse relay R1110, and opens its contacts 932, 934 and 936 to deenergize the two relays R1120 and R3600 and dry the talking circuit as completed between the link 15 and the trunk circuit 27.

When deenergized in response to the operation of the switching relay R930, the relay R3600 opens its contacts 3602 to interrupt one of the circuits for energizing the relay R3510. At its contacts 3601, the relay R3600 prepares the above-mentioned operating circuits for the cut-in relay R3320 and the cut-through relay R2620. At its contacts 3603, the relay R3600 opens a point in the holding circuit for the hold relay R3620. At its contacts 3604, the relay R3600 reprepares the operating circuit for the relay R3520 and recompletes the operating circuit for the relay R3440.

The hold relay R3620, upon restoring, opens its contacts 3622 to deenergize the sender disconnect relay R3630. At its contacts 3621, the relay R3620 interrupts the previously traced circuit for energizing the three relays R3530, R960 and R950 in series. In response to this operation the three relays R960, R970 and R1070 are sequentially released in the trunk circuit 27. The release of these three relays is, however, without effect.

The sender disconnect relay R3630, upon restoring, opens its contacts 3638 to interrupt one of the multiple circuits for energizing the connect relay R3400. At its contacts 3639, the relay R3630 deenergizes the release relay R3610 and the start relay R4350 of the impulse sender 21A. When the start R4350 is thus deenergized, the impulse sender 21A and the operated relays of the digit registers 21B are released in a manner which will be clearly apparent from the above explanation. At its contacts 3634, the relay R3630, upon restoring, completes the prepared one of the operating circuits for the cut-through relay R2620 and the cut-in relay R3320. Thus if the connection has been extended to the toll office No. 2 through the front end of the link 15, i. e., through the call switch 17, the cut-through relay R2620 is energized in response to the release of the sender disconnect relay R3630. On the other hand, if the call has been routed to the toll office No. 2 through the rear end of the link 15, i. e., the answer switch 16, the cut-in relay R3320 is operated in response to the release of the sender disconnect relay R3630. Either of these relays, in operating, locks up and opens the completed start circuit to the sender control circuit 20 in the manner previously explained. Accordingly, when the connect relay R3400 restores in response to the release of the release relay R3610, the operating circuit for the sender start relay R3430 is not recompleted. Upon restoring, the connect relay R3400 opens its contacts 3401 to 3406, inclusive, to disconnect the sender control circuit 20 from the operator position circuit 18 and the link 15. At its contacts 3408, the relay R3400 deenergizes the relays R3440 and R3520. The relay R3520, upon restoring, opens its contacts 3521 and 3522 to deenergize the relay R3510. Following the release of the last-mentioned relay the sender control circuit 20 is fully restored to normal. From the above explanation it will be understood that the register sender 21 and the sender control circuit 20 are automatically released when a flash busy signal is transmitted thereto from the trunk circuit 27 either through the front end or the rear end of the link 15, due

to a blocked switching stage being encountered in the distant office No. 2.

Further to consider the operation of the trunk circuit 27, the position circuit 18, and the link 15, it will be noted that if the cut-through relay R2620 is energized in response to the release of the sender disconnect relay R3630, it closes its contacts 2624 to complete a circuit, including the E. C. control path extending to the trunk circuit 27, over which the front supervisory relay R2600 may be controlled by the supervisory relay R910. This circuit is also prepared at the contacts 1072 when the relays R960, R970 and R1070 are released in the trunk circuit 27 in response to the release of the hold relay R3620. Thus the supervisory relay R910 is rendered operative to transmit ground pulses to the winding of the front supervisory relay R2600 as the flash busy signal is repeated to the relay R910 by the signal relay R820. The supervisory relay R2600, in following the ground pulses, intermittently closes its contacts 2601, thereby to flash the front supervisory lamp 2516. The flash busy signal thus produced by this supervisory lamp informs the operator handling the call at the No. 1 position of the switchboard 11 that a blocked switching stage has been reached at some point in the connection.

If, on the other hand, the cut-in relay R3320 is operated in response to the release of the sender disconnect relay R3630, it opens its contacts 3321 and 3323 to effect the deenergization and release of the dial rear relay R3340. The latter relay, upon restoring, opens the start circuit to the sender control circuit 20, thereby to permit the release of the sender control circuit to proceed, and opens its contacts 3346 to deenergize the dial rear relay R3350. The latter relay, upon restoring, disconnects the sender control circuit 20 from the operator position circuit 18 in the manner previously described. In releasing, the relay R3340 also closes its contacts 3342' to prepare a circuit, including the E. C. control path extending to the trunk circuit 27, over which the rear supervisory relay R3260 may be controlled in accordance with the intermittent operation of the supervisory relay R910 in the trunk circuit 27. In this regard it will be noted that following the operation of the switching relay R930 and the release of the differential slave relay R1070 in the trunk circuit 27, the E. C. control circuit may be traced as extending from ground by way of the contacts 948, 912, 1072 and 1142, C1280, the path through the delayed call selector occupied with the call, the E. C. wiper 2408 of the answer switch 16, the contacts 2441', the normal post springs 2420, the contacts 2531', C2569, the contacts 3342', and the winding of R3260 to battery. This circuit is completed at the contacts 912 to effect the operation of the rear supervisory relay R3260 each time the supervisory relay R910 restores in response to the release of the signal relay R820. The rear supervisory relay R3260, upon operation, closes its contacts 3261 to complete the previously traced circuit including the signal lead C2568 and the contacts 2539 for energizing the rear supervisory lamp 2603. The flashing of this lamp serves to inform the operator handling the call at the No. 1 position of the switchboard 11 that an all-busy condition has been encountered in the extension of the connection and that the connection must be released. The manner in which the operated switches of the train and the front or rear end of the link 15 may be released under

the control of the operator at the switchboard 11 will be clearly apparent from the preceding explanation.

Blocked switching stage in the central office

As previously indicated, provisions may or may not be provided in the switching equipment of the central office 10 for automatically releasing the impulse sending equipment associated with 5 a calling position of the switchboard 11 when a call is routed from the calling position of the switchboard to a selector in the central office 10 at which an all-trunks-busy condition is encountered. With the wiring arrangement thus far 10 considered, no provisions are made for automatically releasing the register sender 21 and the sender control circuit 20 when such a condition is encountered in the extension of a call through the link 15, for example, from the first position 15 of the switchboard 11. In this regard it will be recalled that each of the intermediate toll selectors provided in the central office 10, upon encountering an all-trunks-busy condition, rotates its wipers to the eleventh rotary off-normal 20 positions thereof, switches the talking leads through to an open-circuit and returns flash busy ground pulses at a rate of 120 pulses per minute over the E. C. conductor of its incoming trunk. These ground pulses as transmitted over an established E. C. control path to the sender control circuit 20, for example, will obviously have 25 no effect upon the supervisory relay R3530. This supervisory relay accordingly remains in its restored position when a flash busy signal of the type described is transmitted to the sender control circuit 20 from one of the toll intermediate 30 selectors. Accordingly, the register sender 21 is permitted to continue its operation until all digits registered therein have been transmitted over the established pulsing path to the last operated selector of the train, i. e., the selector in which the all-trunks-busy condition is encountered. The transmission of these digits is obviously 35 without effect since the talking leads of the pulsing circuit are open-circuited in the last selector of the train. After all of the digits have been transmitted, the sender control circuit 20 and the register sender 21 are released in the normal manner. Incident to the release of these two 40 units the cut-through relay of the link, such, for example, as the link 15, occupied with the call at the first position of the switchboard 11, is operated to its switch-through setting wherein the E. C. control path is extended to the front 45 supervisory relay R2600 thereof or to the rear supervisory relay R3260 of the position circuit 18, depending upon whether the call is extended through the front or rear end of the link. With either of these two relays connected to the E. C. 50 control path, the flash busy ground pulses are repeated to the corresponding one of the front and rear supervisory lamps 2516 and 2603 to indicate to the operator that an all-trunks-busy condition has been encountered. Thus it will be 55 noted that with the wiring arrangement thus far considered, the flash busy signal is not received by the operator until the sender 21 occupied with the call clears itself of all digits registered therein and is then released. The interval 60 required for these operations may be substantial if a directory number comprising a large number of digits is keyed into the register sender 21 and an all-trunks-busy condition is encountered after only one or two of the registered digits have 65 been transmitted by the sender.

In order to effect the automatic release of the impulse sending equipment occupied with a call which has been extended to a blocked switching stage in the switching equipment of the central office 10, the Y wiring arrangement as illustrated in Fig. 26 of the drawings may be used. With this wiring arrangement, the 120 I. P. M. lead C2637 is connected to the negative terminal of the exchange battery through the resistor 2684 during the spacing intervals which separate the periods when the pulsing lead C2637 is connected to ground through the commutating segment of the pulsing element 2685. If, with this wiring arrangement, a call is routed through the link 15 to the third selector 34 from the first position of the switchboard 11, and an all-trunks-busy condition is encountered in the selector 34, alternate pulses of ground and negative battery potential are transmitted through the cam springs 2117 from the 120 I. P. M. lead C2637 to the E. C. conductor C2106 of the trunk 34f, after the wipers 2341 to 2346, inclusive, are rotated to the eleventh rotary off-normal positions thereof. More specifically, this pulsing path is completed in response to operation of the switching relay R2120. The negative battery pulses transmitted over the E. C. conductor C2106 are utilized in the sender control circuit 20 to effect the intermittent operation of the supervisory relay R3530. In this regard it will be understood from the preceding explanation that the two relays R3530 and R3520 operate at the beginning of the first received negative battery pulse, the relay R3510 is operated when the relay R3530 releases at the end of the first received battery pulse, and the relay R3440 is operated at the beginning of the second received battery pulse. The last-mentioned relay, upon operating, initiates the release of the register sender 21 and the sender control circuit 20 in the exact manner explained above. In this case, the relay R3600 is not operated in response to the operation of the release relay R3610 since the negative side of the talking circuit, as extended to the wiper 2341 of the selector 34, is disconnected at all points therealong from the negative terminal of the exchange battery. With the relay R3600 in its restored position the locking circuit for the hold relay R3620 is not completed. Accordingly, this hold relay is permitted to release a short time interval following the operation of the release relay R3610. The sender disconnect relay, upon restoring in response to the release of the hold relay R3620, completes the prepared circuit through the contacts 3634, 3611 and 3601 for energizing the cut-through relay R2820 of the link 15 or the cut-in relay R3320 of the position circuit 18, depending upon the direction in which the call was routed to the selector 34 from the first position of the toll switchboard. Either of the two relays R3320 and R2620, upon operating, opens the start circuit to the sender control circuit 20, permitting the release of the sender control circuit to proceed in the exact manner previously explained. It will be noted, moreover, that if the cut-through relay R2620 is operated, the ground pulses as transmitted over the E. C. control path from the selector 34 are utilized to effect the intermittent energization of the front supervisory lamp 2516, whereby the desired flash busy signal is produced. On the other hand, if the cut-in relay R3320 is operated, the ground pulses transmitted over the E. C. control path as extended through the answer switch 16 are utilized to effect the intermittent operation of the rear supervisory relay R3280, whereby the rear

supervisory lamp 2603 is intermittently energized to produce the desired flash busy indication.

EXTENDING A CONNECTION FROM THE SWITCHBOARD 11 THROUGH THE SELECTOR 34

5. Briefly to consider certain additional operating features of the toll selector 34, it is noted that if a call intended for the manual office No. 2, for example, is routed to this selector through the call switch 17 of the link 15 from the No. 1 position of the switchboard 11, the right normal post springs 2312 are operated in the selector 34 in response to vertical movement of the wipers 2341 to 2346, inclusive, to a position opposite the level of contacts in which the trunks extending to the manual office No. 2 are terminated. At the end of the second digit dialed into the toll selector 34 from the register sender, and more particularly when the transfer relays R2230 and R2220 sequentially restore, a circuit including the E. C. control path connecting the selector 34 with the sender control circuit 20 and also including the right normal post springs 2312, is completed for energizing the relay R2310 in series with the supervisory relay R3530 of the sender control circuit. Due to the relatively high resistance of the winding of the supervisory relay R3530, the relay R2310 does not operate when energized in this circuit. Accordingly, the relay R2300 is prevented from operating to connect the negative side of the trunk 34f to the negative terminal of the exchange battery. Thus no circuit is provided for energizing the relay R3600 when the release relay R3610 of the sender control circuit operates. It will be noted in this regard that when energized in series with the relay R2310, the relay R3530 operates to effect the transmission of a stop-indial signal to the register sender 21 in the manner described above. Since, however, the register sender has cleared itself of all digits registered therein, the release of this sender and the sender control circuit may proceed without delay.

In this case the appropriate ringing key 4040 or 4050 may be operated to ring down the selected trunk, such, for example, as the trunk 8, following the seizure of the associated trunk circuit 29 and the switch-through operation of the selector 34. Aside from the fact that manual ringing is in this case utilized to ring down the selected trunk, the various other operations required to complete, supervise, and release the connection are exactly the same as previously explained.

- If the call as extended to the toll selector 34 through the link 15 from the first position of the switchboard 11 is to be routed to its destination through a dial or impulse repeating trunk circuit which requires two digits in the toll selector 34 for the selection thereof, the E. C. wiper 2346 of this selector is connected to ground immediately after the first trunk circuit of the group is selected. Shortly thereafter, and more specifically when the transfer relays R2230 and R2220 release, the operating circuit for the relay R2320 is completed, this circuit extending from the grounded wiper 2346 by way of the contacts 2244, 2228 and 2116, and the winding of R2320 to battery. In operating, the relay R2320 locks to the grounded test conductor C2105 through its contacts 2321. At its contacts 2324, the relay R2320 opens the path for connecting the E. C. conductor C2107 to the E. C. wiper 2346. At its contacts 2323, the relay R2320 opens a point in the operating circuit for the relay R2310. At its contacts 2322, the relay R2320 completes a path through the resistor 2313 for impressing negative battery

potential upon the E. C. conductor C2106. The negative battery potential as applied to the E. C. conductor C2106 constitutes a stop-in-dial or delay send signal which is utilized in the sender control circuit 20 to effect the operation of the relays R3530 and R3520 in the manner previously explained. The relay R3520, upon operating, closes its contacts 3523 to energize the stop send relay R4310 of the impulse sender 21A in the manner pointed out above. Thereafter and when an idle trunk circuit in the selected group is found, the switching relay R2120 is operated to seize the selected trunk circuit and to effect the deenergization of the relay R2240. In releasing, the relay R2240 opens its contacts 2242 to disconnect the E. C. conductor C2106 from the negative terminal of the exchange battery in the selector 34. At its contacts 2243, the relay R2240 connects the E. C. conductor C2106 to the E. C. wiper 2345. This wiper is connected to the negative terminal of the exchange battery in the seized trunk circuit until such time as the connection is extended through this trunk circuit to a numerical switching stage and the numerical switching stage is fully conditioned to accept the impulses of a transmitted digit. At this time ground potential is substituted for negative battery potential upon the E. C. wiper 2345, thereby to effect the release of the supervisory relay R3530. The relay R3530, upon restoring, initiates the previously described operating cycle of the three relays R3510, R3500 and R3520, at the end of which the stop send relay R4310 of the impulse sender 21A is deenergized to condition this sender for further operation. Aside from the fact that the relay R2240 is energized on a call to a two-digit dial trunk circuit, the call is handled in a manner which will be clearly apparent from the foregoing description. In this regard it will be noted that the relay R2240 is deenergized coincident with the deenergization of the switching relay R2120 when the selector preceding the selector 34 is released to disconnect the test conductor C2105 of the trunk 34f from ground.

CALLS FROM THE TOLL SWITCHBOARD 30 TO THE TOLL OFFICE NO. 2

As previously indicated, the toll switchboard 30 is utilized for handling certain of the outward or C. L. R. calls originating in the central office area and routed to the central office switching equipment from one or more tributary exchanges distant from the central office. This switchboard does not, however, receive any inward calls from the distant toll offices or toll centers. In order, however, to provide the necessary facilities for enabling the operators at this switchboard to extend any received C. L. R. call to the desired destination, the different positions of this switchboard are given access to the trunk circuits terminating the trunks extending to the two toll offices and to the two manual offices and also to the interposition trunk circuits associated with the toll switchboard 11. Thus the switchboard 30 is shown as having access to the two-way trunk circuit 26 associated with the trunk 5 extending to the toll office No. 1, the two-way trunk circuit 27 associated with the trunk extending to the toll office No. 2, the ring-down trunk circuit 28 terminating the trunk 7 extending to the manual office No. 1, and the ring-down trunk circuit 29 terminating the trunk 8 which extends to the manual office No. 2. This switchboard is also shown as having access to

the inter-position trunk circuit 24 through which calls may be routed to the first and second positions of the switchboard 11. The relay facilities provided in the trunk circuits 26, 27, 28, 29, and 5 24, to permit the seizure thereof from the switchboard 30, are substantially identical.

To consider the manner in which a call is extended from the switchboard 30 to the toll office No. 2, for example, it may be assumed that the 10 trunk circuit 27 is seized over the trunk 21n from the illustrated position of this switchboard. In order to effect the seizure of the trunk circuit 27 at a time when it is idle, the operator may actuate the key 346 to its off-normal position to complete 15 a circuit for energizing the seizure relay R1260, this circuit extending from ground by way of the contacts 1145 and 1227, the winding of R1260, C1144, the contacts of the key 346, and the resistor 352 to battery. In seizing the trunk 20 circuit 27 the operator initiating the call at the toll switchboard 30 also throws the connect key 355 to its off-normal position to bridge the tip and ring conductors of the position circuit 341 across the talking conductors C1146 and C1148. The operation of the control relay R1030 is without effect.

The relay R1260, upon operating, opens its contacts 1261 to disconnect the test conductor C1279 from the negative terminal of the exchange battery and to interrupt the incomplete operating circuit for the seizure relay R1140. At its contacts 1262, the relay R1260 connects the test conductor C1279 to ground, thereby to mark the trunk circuit 27 as busy in the bank contacts of 30 the selectors to which it is accessible. At its contacts 1263, the relay R1260 completes obvious circuits for energizing the switching relay R1130 and the control relay R1030. At its contacts 1264, the relay R1260 prepares an alternative 35 circuit for energizing the switching relay R930. At its contacts 1265, the relay R1260 opens a point in one of the available circuits for energizing the relay R920. At its contacts 1266, the relay R1260 prepares the operating circuit for the dial relay 40 R1270.

The switching relay R1130, upon operating, 45 performs the functions previously described with reference to the extension of a connection from the toll office No. 1 to the toll office No. 2. In 50 the present case, the series-connected windings of the differential relay R1120 and the loop pulse relay R1110, as bridged across the talking conductors C1148 and C1146 by the switching relay R1130 are energized in series with the winding of 55 a relay provided in the position circuit 341. This loop circuit is not unbalanced when completed through the contacts of the switching relay R1130 and, accordingly, the differential relay R1120 does not operate. The loop pulse relay R1110, however, operates and closes its contacts 1112 to connect the two sides of the trunk 6 to the negative terminal of the exchange battery, whereby the trunk circuit terminating the trunk 6 in the distant toll office No. 2 and an associated selector 60 are seized and conditioned to receive the impulses of the first digit of the directory number designating the desired destination of the call. In operating, the loop pulse relay R1110 also short-circuits the control relay R1030 but the release of the latter relay is without effect. It will also be noted that in this case the switching relay R1130, upon operating, connects the signal lead C1142 to ground through its contacts 1136, 65 whereby a busy lamp at each position of the 70 75

switchboard 30 is energized to indicate the busy condition of the trunk circuit 27. Upon receiving the busy signal indicating that the trunk circuit 27 has been seized, the operator initiating the call at the switchboard 30 may throw the position and trunk keys 343 and 344 to their respective off-normal positions, wherein a circuit is prepared for energizing the digit relay R350 and an obvious circuit is completed for energizing the pulsing relay R360. The pulsing relay R360, upon operating, closes its contacts 361 to prepare a circuit over the pulsing leads C1145 and C1147 for transmitting impulses to the loop pulse relay R1110. After these keys are operated, the operator may actuate the calling device 342 in accordance with the digits of the directory number designating the desired destination of the call. Each time the dial of this device is moved off normal the off-normal springs 342a are closed to energize the digit relay R350 through the contacts of the two keys 343 and 344. In operating, the relay 350 closes its contacts 351 to complete a circuit including the dial lead C1143 and the contacts 1266 for energizing the dial relay R1270. In operating, the dial relay R1270 closes its contacts 1271 and 1273 and then opens its contacts 1272 and 1274, whereby the circuit for energizing the two relays R1110 and R1120 is transferred from the position circuit 341 to the pulsing leads C1147 and C1145, such that the pulsing contacts 361 are included therein. Following this transfer operation, the pulsing relay R360 is rendered operative to repeat the dialed impulses through the contacts 361 to the loop pulse relay R1110. The latter relay, in following the impulses, repeats the same as negative battery and ground pulses over the trunk 6 to the trunk circuit terminating this trunk in the distant toll office No. 2. The battery and ground pulses as received in this trunk circuit are translated into switch directing impulses which are utilized to forward the call to the desired destination. From the above explanation it will be understood that the off-normal springs 342a of the calling device 342 are opened at the end of each digit to effect the sequential release of the digit relay R350 and the dial relay R1270. Accordingly, at the end of the dialing operation the loop circuit through the windings of the loop pulse relay R1110 is connected to include the two talking conductors C1148 and C1146.

When the call is answered at the toll switchboard in the toll office No. 2 or at the called substation, as the case may be, the signal relay R820 is energized to effect the operation of the supervisory relay R910 in the manner previously described. In this case, the relay R910, upon operating, completes a circuit through the contacts 913, 1264 and 1144 for energizing the switching relay R930. The latter relay, upon operating, closes the holding circuit for the loop pulse relay R1110 and dries the loop circuit extending back to the position circuit 341, in a manner which will be clearly apparent from the preceding explanation. In this case, the switching relay R930, upon operating, does not complete its locking circuit through the contacts 931' for the reason that this circuit is now open at the contacts 1143 and 1225. Accordingly, the switching relay R930 is rendered controllable by the supervisory relay R910 and the signal relay R820 to repeat switchhook or flashing recall supervision over the loop circuit extending to the operator position circuit 341. This is accomplished by intermittently including the exchange battery and the series-con-

nected windings of the two relays R1110 and R1120 in the loop circuit to effect the energization of the supervisory relay bridged across this circuit in the operator position circuit 341. In this regard it will be noted that when the called operator or subscriber disconnects to effect the sequential release of the three relays R820, R910 and R930, the windings of the loop pulse relay R1110 and the exchange battery are serially included in the loop circuit which extends to the operator position circuit 341, so that a steady on-hook supervisory signal is produced by the supervisory lamp associated with the connection. If the operator handling the call at the switchboard 30 desires to resign the called subscriber or the called operator, as the case may be, she may do so by operating the ringing key of the position circuit 341 to project ringing current over the dry loop circuit extending to the trunk circuit 27 for the purpose of energizing the rering relay R980. This relay and the companion relays R1010 and R1020 in cooperation with the loop pulse relay R1110, function to transmit a 50-120 millisecond splash of ground potential over the signal lead C1025 and the conductors of the trunk 6 for the purpose of actuating the supervisory relay in the trunk circuit terminating this trunk in the distant toll office. Depending upon the destination of the call, the reoperation of the supervisory relay in the last-mentioned trunk circuit for a measured time interval may be utilized to rering the called operator or substation or to recall the called operator at the toll switchboard in the toll office No. 2.

35 The release of the connection is entirely under the control of the operator handling the call at the switchboard 30. Thus when the connect key 355 and the key 346 are released, the seizure relay R1260 and the loop pulse relay R1110, if operated, are deenergized in an obvious manner. These relays, in restoring, initiate the release of the trunk circuit 27 in a manner which will be clearly apparent from the foregoing explanation. In this regard it is noted that when the loop pulse relay R1110 restores to substitute ground potential for negative battery potential upon the signal lead C1025 and the two conductors of the trunk 6, the trunk circuit terminating the trunk 6 in the distant toll office No. 2 is released to initiate the release of the succeeding switches utilized in extending a connection to the desired destination.

40 While one embodiment of the invention has been disclosed, it will be understood that various modifications may be made therein which are within the true spirit and scope of the invention.

45 What we claim is:

1. In a telephone system, a trunk, a trunk circuit terminating said trunk and including control facilities having two settings wherein received switch directing signals may be repeated over different signal transmitting circuits which respectively include series and parallel arrangements of the talking conductors of said trunk, and means controlled over at least one of the talking conductors of said trunk for determining the setting of said control facilities.

50 2. In a telephone system, a trunk, a trunk circuit terminating said trunk and including control facilities having one setting wherein received switch directing signals may be repeated over a loop signal transmitting circuit which serially includes the talking conductors of said trunk and another setting wherein received switch directing

signals may be repeated over a simplex signal transmitting circuit which includes the talking conductors of said trunk in parallel, and means responsive to the opening of a signal transmitting circuit as established over said trunk to a succeeding switching unit for causing said control facilities to shift from one of its settings to the other.

3. In a telephone system, a trunk, a trunk circuit terminating said trunk and including control facilities having a normal setting wherein received switch directing signals may be repeated over a loop signal transmitting circuit which serially includes the talking conductors of said trunk and another setting wherein received switch directing signals may be repeated over a simplex signal transmitting circuit which includes the talking conductors of said trunk in parallel, and means responsive to the opening of a loop signal transmitting circuit as extended from said trunk to a succeeding switching unit for causing said control facilities to shift to said other setting.

4. In a telephone system, a trunk, signal responsive means operative to repeat received switch directing signals to said trunk, control facilities having one setting wherein received switch directing signals may be repeated by said last-named means over a loop signal transmitting circuit which serially includes the talking conductors of said trunk and another setting wherein received switch directing signals may be repeated by said last-named means over a simplex signal transmitting circuit which includes the talking conductors of said trunk in parallel, and means controlled over at least one of the talking conductors of said trunk for determining the setting of said control facilities.

5. In a telephone system, a trunk, signal responsive means operative to repeat received switch directing signals to said trunk, control facilities having one setting wherein received switch directing signals may be repeated by said last-named means over a loop signal transmitting circuit which serially includes the talking conductors of said trunk and another setting wherein received switch directing signals may be repeated by said last-named means over a simplex signal transmitting circuit which includes the talking conductors of said trunk in parallel, and means responsive to the opening of a signaling circuit which includes the conductors of said trunk for causing said control facilities to shift from one of its two settings to the other.

6. In a telephone system, a trunk, signal responsive means operative to repeat received switch directing signals to said trunk, control facilities having a normal setting wherein received switch directing signals may be repeated by said last-named means over a loop signal transmitting circuit which serially includes the talking conductors of said trunk and another setting wherein received switch directing signals may be repeated by said last-named means over a simplex signal transmitting circuit which includes the talking conductors of said trunk in parallel, and means controlled over at least one of the talking conductors of said trunk for causing said control facilities to shift from said normal setting to said other setting.

7. In a telephone system, a trunk, signal responsive means operative to repeat received switch directing signals to said trunk, control facilities having a normal setting wherein received switch directing signals may be repeated by said last-named means over a loop signal trans-

mitting circuit which serially includes the talking conductors of said trunk and another setting wherein received switch directing signals may be repeated by said last-named means over a simplex signal transmitting circuit which includes the talking conductors of said trunk in parallel, and means responsive to the opening of a loop signal transmitting circuit which includes the talking conductors of said trunk for causing said control facilities to shift from said normal setting to said other setting.

8. In a tandem toll office of an automatic telephone system, a trunk, signal responsive means operative to repeat switch directing signals received from a remote office to said trunk, control facilities having a first setting wherein received switch directing signals may be repeated by said last-named means over a loop signal transmitting circuit which serially includes the talking conductors of said trunk and a second setting wherein received switch directing signals may be repeated over a simplex signal transmitting circuit which includes the talking conductors of said trunk in parallel, and means for controlling said facilities to utilize one setting thereof so long as the extension of a connection involving said trunk is confined to a called point served by said tandem toll office and to cause said facilities automatically to shift to its other setting upon the extension of a connection from said trunk to a second trunk extending to another remote office.

9. In a tandem toll office of an automatic telephone system, a trunk, signal responsive means operative to repeat switch directing signals received from a remote office to said trunk, control facilities having a first setting wherein received switch directing signals may be repeated by said last-named means over a loop signal transmitting circuit which serially includes the talking conductors of said trunk and a second setting wherein received switch directing signals may be repeated over a simplex signal transmitting circuit which includes the talking conductors of said trunk in parallel, and means for controlling said facilities over at least one of the talking conductors of said trunk to utilize one setting thereof so long as the extension of a connection involving said trunk is confined to a called point served by said tandem toll office and to cause said facilities automatically to shift to the other setting thereof upon the extension of a connection from said trunk to a second trunk extending to another remote office.

10. In a tandem toll office of an automatic telephone system, a trunk, signal responsive means operative to repeat switch directing signals received from a remote office to said trunk, control facilities having a normal setting wherein received switch directing signals may be repeated by said last-named means over a loop signal transmitting circuit which serially includes the talking conductors of said trunk and a second setting wherein received switch directing signals may be repeated over a simplex signal transmitting circuit which includes the talking conductors of said trunk in parallel, and means for controlling said facilities to utilize the normal setting thereof so long as the extension of a connection involving said trunk is confined to a called point served by said tandem toll office and to cause said facilities automatically to shift to the other setting thereof upon the extension of a connection from said trunk to a second trunk extending to another remote office.

11. In a tandem toll office of an automatic telephone system, a trunk, signal responsive means operative to repeat switch directing signals received from a remote office to said trunk, control facilities having a normal setting wherein received switch directing signals may be repeated by said last-named means over a loop signal transmitting circuit which serially includes the talking conductors of said trunk and a second setting wherein received switch directing signals may be repeated over a simplex signal transmitting circuit which includes the talking conductors of said trunk in parallel, and means for controlling said facilities over at least one of the talking conductors of said trunk to utilize the normal setting thereof so long as the extension of a connection involving said trunk is confined to a called point served by said tandem toll office and to cause said facilities automatically to shift to the other setting thereof upon the extension of a connection from said trunk to a second trunk extending to another remote office.

12. In a telephone system which includes first and second trunks, the last of which comprises a pair of talking conductors and a control conductor, a trunk circuit connected between said trunks and comprising, in combination, a supervisory relay operative to repeat supervisory signals to said first trunk, control facilities having a first setting wherein switch directing signals received over said first trunk may be repeated over a loop signal transmitting circuit which serially includes the talking conductors of said second trunk and a second setting wherein signals received over said first trunk may be repeated over a simplex signal transmitting circuit which includes the talking conductors of said second trunk in parallel, and means controlled over at least one of the talking conductors of said second trunk for causing said control facilities to shift from one setting to the other and for connecting said supervisory relay to be controlled over the control conductor of said second trunk.

13. In a tandem toll office of an automatic telephone system, a trunk, signal responsive means operative to repeat switch directing signals received from a remote office to said trunk, a supervisory relay operative to transmit supervisory signals to said remote office, control facilities having two settings wherein switch directing signals may be appropriately repeated in either of two different forms over said trunk to succeeding links respectively requiring said two different forms of directive control, means responsive to the extension of a connection from said trunk to a blocked switching stage in said tandem toll office or to the extension of a connection from said trunk to another trunk extending to another remote office for causing said control facilities to shift from one of its two settings to the other, and means operative incident to the shift of said control facilities to said other setting for connecting said supervisory relay to be controlled in accordance with supervisory signals transmitted over said first-named trunk.

14. In a telephone system, first and second trunks, signal responsive means operative to repeat switch directing signals received over said first trunk to said second trunk, a supervisory relay operative to transmit supervisory signals over said first trunk, control facilities having two different settings wherein switch directing sig-

nals may be appropriately repeated by said signal responsive means in either of two different forms to succeeding automatic switching apparatus which may require directive control of said different forms at different switching stages thereof, means responsive to the extension of a connection from said trunk to a blocked switching stage of said apparatus for causing said control facilities to shift from one of its two settings to the other, and means operative incident to the shift of said control facilities to said other setting for connecting said supervisory relay to be controlled in accordance with supervisory signals transmitted over said second trunk.

15. In a telephone system, first and second trunks, signal responsive means operative to repeat switch directing signals received over said first trunk to said second trunk, a supervisory relay operative to transmit supervisory signals over said first trunk, control facilities having two different settings wherein switch directing signals may be appropriately repeater by said signal responsive means in either of two different forms to succeeding automatic switching apparatus which may require directive control of said different forms at different switching stages thereof, means controlled over at least one of the talking conductors of said second trunk and responsive to the extension of a connection from said trunk to a blocked switching stage of said apparatus for causing said control facilities to shift from one of its two settings to the other, and means operative incident to the shift of said control facilities to said other setting for connecting said supervisory relay to be controlled in accordance with supervisory signals transmitted over said second trunk.

16. In a telephone system which includes first and second trunks, a trunk circuit separating said trunks and comprising, in combination, signal responsive means operative to repeat switch directing signals received over said first trunk to said second trunk, a supervisory relay operative to transmit supervisory signals over said first trunk, control facilities having two settings wherein switch directing signals may be appropriately repeated by said signal responsive means in either of two different forms to succeeding automatic switching apparatus which may require directive control of said different forms at different switching stages thereof, means responsive to the extension of a connection from said trunk to a blocked switching stage of said apparatus for causing said control facilities to shift from one of its two settings to the other, and means operative incident to the shift of said control facilities to said other setting for connecting said supervisory relay to be controlled in accordance with supervisory signals transmitted over said second trunk.

17. In a telephone system which includes first and second trunks, a trunk circuit separating said trunk and comprising, in combination, signal responsive means operative to repeat switch directing signals received over said first trunk to said second trunk, a supervisory relay operative to transmit supervisory signals over said first trunk, control facilities having two settings wherein switch directing signals may be appropriately repeated by said last-named means in either of two different forms to succeeding automatic switching apparatus which may require directive control of said different forms at different switching stages thereof, means controlled over at least one of the talking conductors of

said second trunk and responsive to the extension of a connection from said trunk to a blocked switching stage of said apparatus for causing said control facilities to shift from one of its two settings to the other, and means operative incident to the shift of said control facilities to said other setting for connecting said supervisory relay to be controlled in accordance with supervisory signals transmitted over said second trunk.

18. In a telephone system, an exchange including a toll operator switchboard and means including a trunk circuit and automatic switching apparatus for extending a connection from a first remote office to said switchboard or to a second remote office, means in said trunk circuit for repeating switching directing signals received from said first remote office to said apparatus, said trunk circuit also including control facilities having two settings wherein received switch directing signals may be repeated by said signal repeating means to said apparatus over signal transmitting circuits of different forms and a third setting wherein an established signal transmitting circuit is opened in said trunk circuit, means responsive to the extension of a connection from said trunk circuit to a trunk extending to said second remote office for causing said control facilities to shift from one of said two settings to the other, and means responsive to the extension of a connection from said trunk circuit to said switchboard for causing said control facilities to shift to its third setting.

19. In a telephone system, an exchange including a toll operator switchboard and means including a trunk circuit and automatic switching apparatus for extending a connection from a first remote office to said switchboard or to a second remote office, means in said trunk circuit for repeating switch directing signals received from said first remote office to said apparatus, said trunk circuit also including control facilities having two settings wherein received switch directing signals may be repeated by said last-named means to said apparatus over loop and simplex signal transmitting circuits, respectively, and a third setting wherein an established loop signal transmitting circuit is opened in said trunk circuit, means responsive to the extension of a connection from said trunk circuit to a trunk extending to said second remote office for causing said control facilities to shift from one of said two settings to the other, and means responsive to the extension of a connection from said trunk circuit to said switchboard for causing said control facilities to shift to its third setting.

20. In a telephone system which includes switching facilities for extending connections from either of two operator positions to a called point, a supervisory path common to said connections, and supervisory means controllable from said called point to transmit supervisory signals of like significance but different character over said path depending upon the operator position at which a connection including said path is originated.

21. In a telephone system which includes switching facilities for extending connections from either of two operator positions to a called point, a supervisory path common to said connections, and supervisory means operative in response to supervisory operations of like character performed at said called point to transmit

supervisory signals of like significance but different character over said path depending upon the operator position at which a connection including said path is originated.

5 22. In a telephone system which includes switching facilities for non-concurrently extending connections from either of two operator positions to a called point, said connections having a common portion which includes a talking channel and a control path, and supervisory means controllable from said called point to transmit supervisory signals of like significance but different character over said path depending upon the operator position at which a connection including said path is originated.

10 23. In a telephone system which includes switching facilities for non-concurrently extending connections from either of two operator positions to a called point, said connections having a common portion which includes a talking channel and a control path, and supervisory means operative in response to a supervisory operation of one character performed at a called point to transmit a supervisory signal of one character over said control path when a connection including said path is originated at one of said operator positions, said supervisory means also being operative in response to a supervisory operation of said one character performed at a called point to transmit a supervisory signal of different character over said control path when a connection including said path is originated at the other of said operator positions.

20 24. In a telephone system which includes switching facilities for non-concurrently extending connections from either of two operator positions to a called point, said connections including a common trunk, control facilities having two settings respectively corresponding to said operator positions and controlled over said trunk incident to the extension of a connection from either of said operator position over said trunk to assume the setting corresponding to the operator position from which said trunk is seized, and supervisory means controllable from a called point to transmit supervisory signals of like significance but different character over said path depending upon the setting of said control facilities.

35 25. In a telephone system which includes switching facilities for non-concurrently extending connections from either of two operator positions to a called point, said connections having a common trunk which includes a talking channel and a control path, control facilities having two settings respectively corresponding to said operator positions and controlled over said path incident to the extension of a connection from either of said operator positions over said trunk to assume the setting corresponding to the operator position from which said trunk is seized, and supervisory means controllable from a called point to transmit supervisory signals of like significance but different character over said path depending upon the setting of said control facilities.

40 26. In a trunk circuit which includes an access trunk adapted to be seized over either of two different routes, a supervisory path including one of the conductors of said trunk, and supervisory means operative in response to received supervisory signals of like character to transmit supervisory signals of like significance but different character over said path depending upon the route over which said trunk circuit is seized.

27. In a trunk circuit which includes an access trunk adapted to be seized over either of two different routes, a supervisory path including one of the conductors of said trunk, control means having two different settings which respectively correspond to the routes over which said circuit may be seized, and a supervisory relay operative to transmit supervisory signals of like significance but different character over said path depending upon the setting of said control means. 10

28. In a trunk circuit which includes an access trunk adapted to be seized over either of two different routes, a supervisory path including one of the conductors of said trunk, control means having two different settings which respectively correspond to the routes over which said circuit may be seized, and a supervisory relay operative from one of its positions to the other to transmit a call answered or off-hook supervisory signal of one form over said path when said control means occupies one of its settings and operative from said one position to the other to transmit a call answered or off-hook signal of different form over said path when said control means occupies the other of its settings. 15

29. In a trunk circuit which includes an access trunk adapted to be seized over either of two different routes, a supervisory path including one of the conductors of said trunk, control means having two different settings which respectively correspond to the routes over which said trunk may be seized, means controlled over said path incident to the extension of a connection by way of said trunk for causing said control means to assume the setting corresponding to the route over which said trunk is seized, and supervisory means operative in response to received supervisory signals of like character to transmit supervisory signals of like significance but different character over said path depending upon the setting of said control means. 20

30. In a trunk circuit which includes an access trunk adapted to be seized over either of two different routes, a supervisory path including one of the conductors of said trunk, control means having two different settings which respectively correspond to the routes over which said trunk may be seized, means comprising a marginal relay which is controlled over said path incident to the extension of a connection by way of said trunk for causing said control means to assume the setting corresponding to the route over which said trunk is seized, and supervisory means operative in response to received supervisory signals of like character to transmit supervisory signals of like significance but different character over said path depending upon the setting of said control means. 25

31. In a trunk circuit which includes an access trunk adapted to be seized over either of two different routes and wherein said trunk includes two conductors defining a talking channel, a test conductor and a supervisory conductor, control means having two different settings which respectively correspond to the routes over which said trunk may be seized, means controlled over said supervisory conductor incident to the extension of a connection by way of said trunk for causing said control means to assume the setting corresponding to the route over which said trunk is seized, and supervisory means operative in response to received supervisory signals of like character to transmit supervisory signals of like 30

significance but different character over said supervisory conductor depending upon the setting of said control means.

32. In a trunk circuit which includes an access trunk adapted to be seized over either of two different routes and wherein said trunk includes two conductors defining a talking channel, a test conductor and a supervisory conductor; control means having two different settings which respectively correspond to the routes over which said trunk may be seized, means comprising a marginal relay which is controlled over said supervisory conductor incident to the extension of a connection by way of said trunk for causing said control means to assume the setting corresponding to the route over which said trunk is seized, and supervisory means operative in response to received supervisory signals of like character to transmit supervisory signals of like significance but different character over said supervisory conductor depending upon the setting of said control means. 35

33. In a telephone system which includes two toll operator switchboards requiring different types of supervisory signals to indicate like supervisory operations in the supervision of connections non-concurrently established between said switchboards and a remote point over a partially common channel, a supervisory path included in 40 said common channel, means controllable from said remote point to transmit supervisory signals over said path to either of said switchboards, and means for making the type of supervisory signals transmitted by said last-named means over said path conform to the supervisory requirements of the switchboard to which they are transmitted. 35

34. In a telephone system which includes two toll operator switchboards requiring different types of supervisory signals to indicate like supervisory operations in the supervision of connections non-concurrently established between said switchboards and a remote point over a partially common channel, a supervisory path included in 45 said common channel, means controllable from said remote point to transmit supervisory signals over said path to either of said switchboards, and means automatically controlled incident to the establishing of a connection which includes said common channel and involves either of said switchboards for making the type of supervisory signals transmitted by said last-named means over said path conform to the supervisory requirements of the switchboard to which they are transmitted. 50

35. In a telephone system which includes two toll operator switchboards requiring different types of supervisory signals to indicate like supervisory operations in the supervision of connections non-concurrently established between said 55 switchboards and a remote point over a partially common channel, a supervisory path included in said common channel, means controllable from said remote point to transmit supervisory signals over said path to either of said switchboards, and means automatically controlled over said path incident to the establishing of a connection which includes said common channel and involves either of said switchboards for making the type of supervisory signals transmitted by said last-named means over said path conform to the supervisory requirements of the switchboard to which they are transmitted. 60

36. In a telephone system which includes two toll operator switchboards requiring different types of supervisory signals to indicate like 75

perisory operations in the supervision of connections which may be non-concurrently extended from said switchboards to a remote point over a partially common channel, a supervisory path included in said common channel, means controllable from said remote point to transmit supervisory signals over said path to either of said switchboards, and means automatically controlled incident to the extension of a connection over said channel from either of said switchboards for making the type of supervisory signals transmitted by said last-named means over said path conform to the supervisory requirements of the switchboard to which they are transmitted.

37. In a telephone system which includes two toll operator switchboards requiring different types of supervisory signals to indicate like supervisory operations in the supervision of connections which may be nonconcurrently extended from said switchboards to a remote point over a partially common channel, a supervisory path included in said common channel, means controllable from said remote point to transmit supervisory signals over said path to either of said switchboards, and means automatically controlled over said path incident to the extension of a connection over said channel from either of said switchboards for making the type of supervisory signals transmitted by said last-named means over said path conform to the supervisory requirements of the switchboard to which they are transmitted.

38. In a trunk circuit which includes an access trunk adapted to be seized over either of two different routes, an outgoing trunk and facilities for repeating switch directing signals received over said access trunk from a register sender to said outgoing trunk; a combination supervisory and sender control path including one of the conductors of said access trunk, control facilities having a sender control setting and two different supervisory settings which respectively correspond to said two different routes, and means controllable over said outgoing trunk to transmit sender control signals over said path so long as said control facilities occupy the sender control setting thereof and also operative in response to received supervisory signals of like character to transmit supervisory signals of like significance but different character over said path when said control facilities occupy different ones of the supervisory settings thereof.

39. In a trunk circuit which includes an access trunk adapted to be seized over either of two different routes, an outgoing trunk and facilities for repeating switch directing signals received over said access trunk from a register sender to said outgoing trunk; a combination supervisory and sender control path including one of the conductors of said access trunk, control facilities having a sender control setting and two different supervisory settings which respectively correspond to said two different routes, means controllable over said access trunk for selectively determining the setting of said control facilities, and means controllable over said outgoing trunk to transmit sender control signals over said path so long as said control facilities occupy the sender control setting thereof and also operative in response to received supervisory signals of like character to transmit supervisory signals of like significance but different character over said path when said control facilities occupy different ones of the supervisory settings thereof.

40. In a trunk circuit which includes an access

trunk adapted to be seized over either of two different routes, an outgoing trunk and facilities for repeating switch directing signals received over said access trunk from a register sender to said outgoing trunk; a combination supervisory and sender control path including one of the conductors of said access trunk, control facilities having a sender control setting and two different supervisory settings which respectively correspond to said two different routes, means comprising a margined relay which is marginally controlled over said path in accordance with the route over which said access trunk is seized for selectively determining the setting of said control facilities, and means controllable over said outgoing trunk to transmit sender control signals over said path so long as said control facilities occupy the sender control setting thereof and also operative in response to received supervisory signals of like character to transmit supervisory signals of like significance but different character over said path when said control facilities occupy different ones of the supervisory settings thereof.

25 41. In a trunk circuit which includes an access trunk adapted to be seized over either of two different routes, an outgoing trunk and facilities for repeating switch directing signals received over said access trunk from a register sender to said outgoing trunk; a combination supervisory and sender control path including one of the conductors of said access trunk, control facilities having a sender control setting and two different supervisory settings which respectively correspond to said two different routes, means responsive to the seizure of said circuit over one of said routes for shifting said control facilities from its sender control setting to the supervisory setting corresponding to said one route, and means controllable over said outgoing trunk to transmit sender control signals over said path so long as said control facilities occupy the sender control setting thereof and also operative in response to received supervisory signals of like character to transmit supervisory signals of like significance but different character over said path when said control facilities occupy different ones of the supervisory settings thereof.

30 42. In a trunk circuit which includes an access trunk adapted to be seized over either of two different routes, an outgoing trunk and facilities for repeating switch directing signals received over said access trunk from a register sender to said outgoing trunk; a combination supervisory and sender control path including one of the conductors of said access trunk, control facilities having a sender control setting and two different supervisory settings which respectively correspond to said two different routes, means controlled over a connection routed over one of said two routes by the register sender associated with the connection for shifting said control facilities from its sender control setting to the supervisory setting corresponding to said one route after the sender has cleared itself of at least a portion of the digits registered therein, and means controllable over said outgoing trunk to transmit sender control signals over said path so long as said control facilities occupy the sender control setting thereof and also operative in response to received supervisory signals of like character to transmit supervisory signals of like significance but different character over said path when said control facilities occupy different ones of the supervisory settings thereof.

43. In a trunk circuit which includes an access trunk adapted to be seized over either of two different routes, an outgoing trunk and facilities for repeating switch directing signals received over said access trunk from a register sender to said outgoing trunk; a combination supervisory and sender control path including one of the conductors of said access trunk, control facilities having a sender control setting and two different supervisory settings which respectively correspond to said two different routes, means responsive to the seizure of said circuit over one of said routes for shifting said control facilities from its sender control setting to the supervisory setting corresponding to said one route, means controllable over a connection routed over the other of said routes by the register sender associated with the connection for shifting said control facilities from its sender control setting to the supervisory setting corresponding to said other route after the sender has cleared itself of at least a portion of the digits registered therein, and means controllable over said outgoing trunk to transmit sender control signals over said path so long as said control facilities occupy the sender control setting thereof and also operative in response to received supervisory signals of like character to transmit supervisory signals of like significance but different character over said path when said control facilities occupy different ones of the supervisory settings thereof.

44. In a trunk circuit which terminates an outgoing trunk and includes an access trunk adapted to be seized over either of two different routes, a signal repeating relay controllable over said access trunk to repeat switch directing and supervisory signals over said outgoing trunk, an alternating current supervisory relay adapted to be controlled over said access trunk and operative to control said signal repeating relay, control means having two different settings which respectively correspond to the routes over which said circuit may be seized, a supervisory path including one of the conductors of said trunk, supervisory means operative in response to supervisory signals of like character received over said outgoing trunk for transmitting supervisory signals of like significance but different character over said path depending upon the setting of said control means, and means responsive to operation of said control means to one of its two settings for connecting said alternating current relay to be controlled over said access trunk, rendering said signal repeating relay noncontrollable directly over said trunk and rendering said signal repeating relay controllable by said alternating current relay.

45. In a trunk circuit which terminates an outgoing trunk and includes an access trunk adapted to be seized over either of two different routes, a pair of signal repeating relays respectively corresponding to said routes and each controllable over said access trunk to repeat switch directing and supervisory signals to said outgoing trunk, an alternating current supervisory relay adapted to be controlled over said access trunk and operative to control one of said signal repeating relays, control means having two different settings which respectively correspond to the routes over which said circuit may be seized, a supervisory path including one of the conductors of said access trunk, supervisory means operative in response to supervisory signals of like character received over said outgoing trunk for transmitting supervisory signals of like significance but

different character over said path depending upon the setting of said control means, means responsive to operation of said control means to one of its two settings for connecting the other of said signal repeating relays to be controlled over said access trunk, and means responsive to operation of said control means to the other of its two settings for connecting said alternating current relay to be controlled over said access trunk, rendering said one signal repeating relay noncontrollable directly over said trunk and rendering said one signal repeating relay controllable by said alternating current relay.

46. In a trunk circuit which terminates an outgoing trunk and includes an access trunk adapted to be seized over either of two different routes, a pair of signal repeating relays respectively corresponding to said routes and each controllable over said access trunk to repeat switch directing and supervisory signals to said outgoing trunk, an alternating current supervisory relay adapted to be controlled over said access trunk and operative to control one of said signal repeating relays, control means having two different settings which respectively correspond to the two routes over which said circuit may be seized, means responsive to operation of said control means to one of its two settings for connecting the other of said signal repeating relays to be controlled over said access trunk, and means responsive to operation of said control means to the other of its two settings for connecting said alternating current relay to be controlled over said access trunk, rendering said one signal repeating relay noncontrollable directly over said access trunk and rendering said one signal repeating relay controllable by said alternating current relay.

47. In a trunk circuit which terminates an outgoing trunk and includes an access trunk adapted to be seized over either of two different routes, a pair of signal repeating relays respectively corresponding to said routes and each controllable over said access trunk to repeat switch directing signals to said outgoing trunk, and means selectively controllable over said access trunk in accordance with the route over which said circuit is seized for selecting the correct one of said relays for use in repeating switch directing signals to said outgoing trunk.

48. In a trunk circuit which terminates an outgoing trunk and includes an access trunk adapted to be seized over either of two different routes, said access trunk including a pair of talking conductors, a test conductor and a fourth conductor, a pair of signal repeating relays respectively corresponding to said routes and respectively controllable over series and parallel arrangements of the talking conductors of said access trunk to repeat switch directing signals to said outgoing trunk, and means selectively controlled over said fourth conductor in accordance with the route over which said circuit is seized for selecting the correct one of said relays for use in repeating switch directing signals to said outgoing trunk.

49. In a trunk circuit which terminates an outgoing trunk and includes an access trunk, a signal repeating relay controllable over said access trunk to repeat switch directing and supervisory signals to said outgoing trunk, an alternating current supervisory relay adapted to be controlled over said access trunk and operative to control said signal repeating relay, and means controllable over said access trunk for connecting said alternating current relay to be controlled over

said access trunk, rendering said signal repeating relay noncontrollable directly over said access trunk and rendering said signal repeating relay controllable by said alternating current relay.

50. In a trunk circuit which terminates an outgoing trunk and includes an access trunk, said access trunk including a pair of talking conductors, a test conductor and a fourth conductor, a signal repeating relay controllable over the talking conductors of said access conductors to repeat switch directing and supervisory signals to said outgoing trunk, an alternating current supervisory relay adapted to be controlled over one of the talking conductors of said access trunk and operative to control said signal repeating relay, and means controllable over said fourth conductor for connecting said alternating current relay to be controlled over said access trunk, rendering said signal repeating relay noncontrollable over the talking conductors of said access trunk and rendering said signal repeating relay controllable by said alternating current relay.

51. In a telephone system which includes a register sender operative to direct the operation of automatic switching apparatus in the extension of a connection from a calling point to a called point, a trunk circuit controllable by said sender and having one setting wherein switch directing signals transmitted thereto from said sender may be repeated to succeeding automatic switching apparatus and a second setting wherein supervisory signals may be repeated in at least one direction between the calling and called points, means for extending a connection from said sender to said trunk circuit, said connection comprising a loop circuit over which switch directing signals may be transmitted, means responsive to the extension of said connection to said trunk circuit for causing said trunk circuit to assume said one setting, means controlled by said sender for unbalancing said loop circuit, and means responsive to the unbalancing of said loop circuit for causing said trunk circuit to shift to said second setting.

52. In a telephone system which includes a register sender operative to direct the operation of automatic switching apparatus in the extension of a connection from a calling point to a called point, a trunk circuit controllable by said sender and having one setting wherein switch directing signals transmitted thereto from said sender may be repeated to succeeding automatic switching apparatus and a second setting wherein supervisory signals may be repeated in at least one direction between the calling and called points, means controlled by said sender for extending a connection from said sender to said trunk circuit, said connection comprising a loop circuit over which switch directing signals may be transmitted, means responsive to the extension of said connection to said trunk circuit for causing said trunk circuit to assume said one setting, means controlled by said sender for unbalancing said loop circuit, and means responsive to the unbalancing of said loop circuit for causing said trunk circuit to shift to said second setting.

53. In a telephone system, a trunk circuit, an

incoming trunk line terminating in said trunk circuit, an automatic switch, means for seizing said trunk circuit and extending a connection thereto over said incoming trunk line, means for transmitting impulses over said incoming trunk line to control said automatic switch to seize either of two paths to further extend said connection, and means in said trunk circuit controlled from the seized path for causing the impulses transmitted over said seized path thereafter to be of one form or another, dependent on the path seized.

54. In a telephone system, an incoming trunk circuit, local subscriber lines, an outgoing trunk circuit, means for transmitting impulses to said incoming trunk circuit, automatic switches controlled by the impulses transmitted to said incoming trunk for extending a connection either to a local subscriber or to said outgoing trunk circuit, means in said incoming trunk circuit for repeating impulses transmitted to said switches in one form in the event the connection is extended to a local subscriber, and means in said incoming trunk circuit operated on seizure of said outgoing trunk circuit to further extend the connection for altering the form of the subsequent impulses transmitted to said outgoing trunk circuit.

55. In a telephone system, a trunk line, an incoming trunk circuit terminating said trunk line, an automatic switch, means for transmitting impulses over said trunk line, means in said incoming trunk circuit for repeating said impulses to said switch to extend a connection, a first path, a second path including an outgoing trunk circuit, means in said incoming trunk circuit for repeating said impulses in one form to further extend said connection over said first path, and means in said incoming trunk circuit operated in the event said outgoing trunk circuit is selected over said second path for disconnecting the impulse repeating means in said incoming trunk circuit and causing subsequent impulses received over said trunk line to be repeated by said outgoing trunk circuit to further extend said connection over said second path.

56. In a telephone system, a trunk line, an incoming trunk circuit terminating said trunk line, an automatic switch, a first path accessible to said switch, a second path including an outgoing trunk circuit accessible to said switch, means for transmitting impulses over said trunk line, means in said incoming trunk circuit for repeating said impulses to said switch thereby to operate said switch to select said first or said second path to extend a connection, means in said incoming trunk circuit operated under control of said outgoing trunk circuit in the event said second path is seized for disconnecting said incoming trunk circuit impulse repeating means and causing impulses received over said trunk line to be repeated by said outgoing trunk circuit to further extend said connection.
